(57) **ABSTRACT**
A drilling mud screen comprising a first body having a first end and a second end and a first centerline, a filter having a first end, a second end, and openings, wherein the second end of the filter is fluidly connected to the first end of the first body via a first connection and/or an optional first end retaining ring, a first end cap fluidly connected at the first end of the filter via a second connection, wherein the filter has an optional retaining ring disposed between the first connection and the second connection a drilling mud inlet at the openings of the filter, and a drilling mud outlet at the second end of the first body is disclosed. Methods of installing and using the drilling mud screen system are also disclosed.

FIELD OF INVENTION

The present invention relates generally to an improved drilling mud screen system and methods thereof and, more particularly, to an improved, piston-style drilling mud screen system with a drilling mud screen puller/installer tool and methods thereof.

BACKGROUND OF THE INVENTION

Many drilling rigs use drill pipe mud screens that are in-line with the drilling assembly. Typically, drilling mud screens, commonly Type 3 drilling mud screens, are installed on the drill floor or at the bottom of the drill string. If the drilling mud screen is installed on the drill floor, the drilling mud screen must be reinstalled or replaced every time a section of stand pipe is added to the drill string. In other words, the drilling mud screens must be installed at the top of each 90-foot stand of pipe above the rig crew. As each stand of drill pipe is drilled down to the derrick floor, the top drive sub-connection is separated from the drill pipe stand connection and the drilling mud screen is installed to the top of the next stand of pipe going in the hole. This is a dangerous practice that can result in accidents to the crew below.

Although the Type 3 drilling mud screen appears to work for single-shoulder API rotary shouldered connection types, it does not work for proprietary double-shoulder high-strength connection types that eliminate the space where the drilling mud screen is typically located inside the pipe. Instead, the nose of the double-shoulder pin connection on the top of the drive sub-connection is decreased to the exact width of the drilling mud screen flange, so that “theoretically” the nose of the double-shoulder pin connection may have the same contact inside the mating drill pipe box and

2

same shoulder bearing stress at optimal connection make-up torque as it would in an unmodified assembly. Further, the dimensions of the shortened nose of the double-shoulder pin may not be adequate for the selected drilling mud screen flange. When the dimensions of the shortened nose of the double-shoulder pin are outside the acceptable connection tolerances of about ± 0.000 -inch to about ± 0.0010 -inch, the mating pin and/or box is damaged. Further, rig crews often forget to install the drilling mud screen. This oversight frequently results in damage as the shortened nose of the double-shoulder pin continuously tries to make-up inside the box but fails. These are dangerous practices that can result in drilling mud leaking onto the drilling rig floor creating a slip hazard and/or in a double-shoulder connection failure. Further, this is an expensive practice that rapidly consumes drilling mud screens long before they need to be replaced.

If the drilling mud screen is installed at the bottom of the drill string, the drilling mud screen must be brought to the surface to be replaced. This is an inefficient practice that can result in lost drilling time.

Thus, an improved drilling mud screen system with a drilling mud screen puller/installer tool is needed to eliminate these problems.

SUMMARY OF THE INVENTION

In an embodiment, a drilling mud screen system comprises a first body having a first drilling mud inlet, an optional first drilling mud inlet, a first drilling mud outlet and a drilling mud screen access port, an optional drilling mud screen insert, a drilling mud screen, and a first end cap.

In an embodiment, the first body has a first end, a second end and a first centerline from the first end to the second end.

In an embodiment, the first drilling mud inlet has a second centerline forming a first angle with the first centerline and extending to the first centerline, wherein the first drilling mud inlet is offset from the first end of the first body. In an embodiment, the first angle is from about 20-degrees to about 120-degrees.

In an embodiment, the optional first drilling mud inlet has an optional second centerline forming an optional first angle with the first centerline and extending to the first centerline and forming an optional second angle with the second centerline, wherein the optional first drilling mud inlet is offset from the first end of the first body and wherein the optional first drilling mud inlet is offset from the second centerline radially about the first centerline. In an embodiment, the optional first angle is from about 20-degrees to about 120-degrees.

In an embodiment, the first drilling mud outlet is at the second end of the first body.

In an embodiment, the drilling mud screen access port is at the first end of the first body. In an embodiment, the first end cap is disposed within the drilling mud access port to close and seal the drilling mud access port.

In an embodiment, the drilling mud screen is disposed within the first body between the first drilling mud inlet and the first drilling mud outlet.

In an embodiment, the drilling mud screen comprises a second body having a second drilling mud inlet, a second drilling mud outlet, a second end cap and a filter.

In an embodiment, the drilling mud screen is constructed from AISI 4145 or equivalent, stainless steel or combinations thereof. In an embodiment, the filter has a hardened coating.

In an embodiment, the optional drilling mud screen insert is disposed within the first body between the first drilling mud inlet and the drilling mud screen.

In an embodiment, the second body has a first end and a second end, wherein the first end and/or the second end of the body has a means to engage a drilling mud screen puller/installer tool.

In an embodiment, the second drilling mud inlet is at the first end of the second body.

In an embodiment, the filter has a first end, a second end, and openings, wherein the filter is fluidly connected to the second end of the second body via a first connection and/or an optional first end retaining ring. In an embodiment, the filter is straight or tapered from the first end to the second end of the filter. In an embodiment, the filter is tapered from the first end to the second end of the filter.

In an embodiment, the filter comprises a plurality of rods having a first end and a second end, wherein the rods are spaced a distance apart to form the openings in the filter. In an embodiment, the rods are tapered from the first end to the second end of the filter.

In an embodiment, the filter comprises a formed sheet having drilled holes or slots spaced a distance apart to form the openings in the filter. In an embodiment, the drilled holes or slots are drilled in any configuration and orientation from the first end to the second end of the filter. In an embodiment, the drilled holes or slots are drilled in offset rows or straight rows from the first end to the second end of the filter.

In an embodiment, the second drilling mud outlet is at the openings of the filter.

In an embodiment, the second end cap is fluidly connected at the second end of the filter via a second connection. In an embodiment, the filter has an optional retaining ring disposed between the first connection and the second connection.

In an embodiment, the first body comprises a third body and a fourth body, and wherein the third body is fluidly connected to the fourth body via a union.

In an embodiment, one or more of the first body, the second body, the third body and the fourth body are constructed from AISI 4130/75k or equivalent material, AISI 4145 or equivalent, or combinations thereof.

In an embodiment, the first body has a first portion and a second portion surrounding the filter, and wherein a second inner diameter of the second portion is larger than a first inner diameter of the first portion to provide a high flow rate of drilling mud through the filter.

In an embodiment, the second end cap is a flat plate or a flat plate with holes or slots. In an embodiment, the second end cap is an inverted cone or an inverted cone with holes or slots.

In an embodiment, the first centerline of the first body and an inner surface of the second end cap form a cap angle, wherein the cap angle is from about 30-degrees to about 60-degrees. In an embodiment, the first centerline of the first body and an inner surface of the second end cap form a cap angle, wherein the cap angle is from about 35-degrees to about 45-degrees.

In an embodiment, a drilling mud screen system, comprises a first body having a first drilling mud inlet, a first drilling mud outlet and a drilling mud screen access port, a drilling mud screen, a plug and a first end cap.

In an embodiment, the first body has a first end, a second end and a first centerline from the first end to the second end.

In an embodiment, the first drilling mud inlet has a second centerline forming a first angle with the first centerline and

extending to the first centerline, wherein the first drilling mud inlet is offset from the first end of the first body.

In an embodiment, the first drilling mud outlet is at the second end of the first body.

In an embodiment, the drilling mud screen access port is at the first end of the first body. In an embodiment, the first end cap is disposed within the drilling mud access port to close and seal the drilling mud access port.

In an embodiment, the first end cap is disposed within the drilling mud access port to close and seal the drilling mud access port.

In an embodiment, the plug is disposed within the first body between the drilling mud access port and the first drilling mud inlet.

In an embodiment, the drilling mud screen is disposed within the first body between the first drilling mud inlet and the first drilling mud outlet.

In an embodiment, the drilling mud screen comprises a second body having a second drilling mud inlet, a second drilling mud outlet, a second end cap and a filter.

In an embodiment, the drilling mud screen is constructed from AISI 4145 or equivalent, stainless steel or combinations thereof. In an embodiment, the optional drilling mud screen insert, the optional first end retaining ring and/or the optional retaining ring is constructed from AISI 4145 or equivalent, stainless steel or combinations thereof and/or has a hardened coating. In an embodiment, the filter has a hardened coating.

In an embodiment, the second body has a first end and a second end, wherein the first end and/or the second end of the body has a means to engage a drilling mud screen puller/installer tool.

In an embodiment, the second drilling mud inlet is at the first end of the second body.

In an embodiment, the filter has a first end, a second end, and openings, wherein the filter is fluidly connected to the second end of the second body. In an embodiment, the filter is straight or tapered from the first end to the second end of the filter. In an embodiment, the filter is tapered from the first end to the second end of the filter.

In an embodiment, the filter comprises a plurality of rods having a first end and a second end, wherein the rods are spaced a distance apart to form the openings in the filter. In an embodiment, the rods are tapered from the first end to the second end of the filter.

In an embodiment, the filter comprises a formed sheet having drilled holes or slots spaced a distance apart to form the openings in the filter. In an embodiment, the drilled holes or slots are drilled in any configuration and orientation from the first end to the second end of the filter. In an embodiment, the drilled holes or slots are drilled in offset rows or straight rows from the first end to the second end of the filter.

In an embodiment, the second drilling mud outlet is at the openings of the filter.

In an embodiment, the end cap is fluidly connected at the second end of the filter.

In an embodiment, the plug comprises a third body having a first end and a second end, wherein the first end of the third body has a means to engage a drilling mud screen puller/installer tool.

In an embodiment, the first end of the third body has an optional cavity extending towards but not through the flow surface of the plug.

In an embodiment, the third body has an optional port extending from an outer surface of the plug into the optional cavity.

In an embodiment, the second end of the third body has a flow surface to direct the drilling mud from the first drilling mud inlet to the second drilling mud inlet. In an embodiment, the flow surface may be selected from the group consisting of a backwards "J" shape, a curved shape, an "L" shape and combinations and variations thereof.

In an embodiment, one or more of the first body, the second body and the third body are constructed from AISI 4130/75k or equivalent material, AISI 4145 or equivalent, or combinations thereof.

In an embodiment, the first body has a first portion and a second portion surrounding the filter, and wherein a second inner diameter of the second portion is larger than a first inner diameter of the first portion to provide a high flow rate of drilling mud through the filter.

In an embodiment, the second end cap is a flat plate or a flat plate with holes or slots. In an embodiment, the second end cap is an inverted cone or an inverted cone with holes or slots.

In an embodiment, the first centerline of the first body and an inner surface of the second end cap form a cap angle, wherein the cap angle is from about 30-degrees to about 60-degrees. In an embodiment, the first centerline of the first body and an inner surface of the second end cap form a cap angle, wherein the cap angle is from about 35-degrees to about 45-degrees.

In an embodiment, the drilling mud screen system further comprises a transducer subassembly. In an embodiment, the transducer subassembly comprises a body having a drilling mud inlet, a drilling mud outlet and a transducer access port, and a transducer.

In an embodiment, the body has a first end, a second end and a first centerline from the first end to the second end.

In an embodiment, the drilling mud inlet is at the first end of the body.

In an embodiment, the first drilling mud outlet is at the second end of the first body.

In an embodiment, the transducer access port has a second centerline forming a transducer angle with the first centerline and extending to the first centerline, wherein the transducer access port is offset from the first end of the body. In an embodiment, the transducer angle is from about 20-degrees to about 120-degrees.

In an embodiment, the transducer is disposed within the transducer access port to close and seal the transducer access port.

In an embodiment, the drilling mud outlet of the transducer assembly is fluidly connected to the first drilling mud inlet of the drilling mud screen system.

In an embodiment, a drilling mud screen puller/installer tool comprises a hollow body, a striker plate, a shaft having a puller/installer plate and an optional stop plate, groove or painted line, a movable sleeve disposed around a portion of the shaft, and a handle.

In an embodiment, the hollow body has a first end, a second end and a first length.

In an embodiment, the striker plate has a first end and a second end, wherein the first end striker plate is connected to the second end of the body via a first connection.

In an embodiment, the shaft has a first end, a second end and a second length, wherein the second end of the striker plate is connected to the first end of the shaft via a second connection.

In an embodiment, the puller/installer plate has a first end and a second end, wherein the second end of the shaft is connected to the first end of the puller/installer plate via a fourth connection. In an embodiment, the puller/installer

plate has a means to engage a drilling mud screen. In an embodiment, the puller/installer plate has one or more extensions to fit an outlet of a first portion and/or an inlet of a second portion of the body of the drilling mud screen and to rotationally engage a shoulder inside the inlet of the second portion of the body of the drilling mud screen.

In an embodiment, the optional stop plate, groove or painted line on the shaft is offset from the first end of the body or the second end of the body. In an embodiment, the stop plate is connected to the shaft via a fifth connection.

In an embodiment, the movable sleeve has a first end, a second end and a third length, wherein the movable sleeve is disposed around a portion of the shaft.

In an embodiment, the handle is connected to the movable sleeve via a third connection.

In an embodiment, one or more of the first, second, third, fourth and fifth connections are welds.

In an embodiment, one or more of the body and the movable sleeve are constructed from AISI 4140 or equivalent, stainless steel or combinations thereof.

In an embodiment, one or more of the handle and the shaft are constructed from AISI 1018 or equivalent.

In an embodiment, one or more of the rounded end, the striker plate and the puller/installer plate are constructed from stainless steel.

In an embodiment, a method of installing a drilling mud screen system comprises a) providing a drilling mud screen system, b) stopping a drilling mud pump to fluidly connect the drilling mud screen to the drilling mud pump, c) fluidly connecting the drilling mud screen system in line with and immediately upstream or downstream of the drilling mud pump; and d) operating the drilling mud pump to produce flow of drilling mud through the drilling mud screen system.

In an embodiment, step c) comprises fluidly connecting a drilling mud inlet of the drilling mud screen system to a high-pressure outlet of the drilling mud pump and fluidly connecting a drilling mud outlet of the drilling mud screen system to a vibrator hose or a standpipe.

In an embodiment, step c) comprises fluidly connecting a drilling mud inlet of the drilling mud screen system to a high-pressure inlet of the drilling mud pump and fluidly connecting a drilling mud outlet of the drilling mud screen system to an inlet of a vibrator hose.

In an embodiment, step c) comprises fluidly connecting a drilling mud inlet of the drilling mud screen system to an outlet of a vibrator hose and a drilling mud outlet to an inlet of a standpipe.

In an embodiment, step c) comprises fluidly connecting a drilling mud inlet of the drilling mud screen system to an outlet of a first portion of a standpipe and a drilling mud outlet to an inlet of a second portion of the standpipe.

In an embodiment, step e) comprises filtering or screening debris from drilling mud.

In an embodiment, a method of installing and using a drilling mud screen system comprises: a) providing the drilling mud screen system; b) stopping a drilling mud pump; c) fluidly connecting a first transducer subassembly, having a transducer, in line with and downstream of the drilling mud pump and fluidly connecting the drilling mud screen system in line with and immediately downstream of the first transducer subassembly; and d) operating the drilling mud pump to produce flow of drilling mud through the first transducer subassembly and the drilling mud screen system.

In an embodiment, the method further comprises step (e) monitoring the transducer of the first transducer subassembly for property information immediately upstream of the

drilling mud screen system and step (f) using the property information to determine a status of the drilling mud screen system.

In an embodiment, step (c) comprises fluidly connecting a first transducer subassembly, having a transducer, in line with and downstream of the drilling mud pump and fluidly connecting the drilling mud screen system in line with and immediately downstream of the first transducer subassembly, and fluidly connecting a gate valve in line with and immediately downstream of the drilling mud screen system, fluidly connecting a second transducer assembly, having a low torque plug valve, in line with and immediately downstream of the gate valve and wherein step (d) comprises operating the drilling mud pump to produce flow of drilling mud through the first transducer subassembly, the drilling mud screen system, the gate valve and the second transducer subassembly.

In an embodiment, the method of claim 78 further comprises step (e) stopping the drilling mud pump, step (f) closing the gate valve to isolate the drilling mud screen system, and step (g) pumping cement through the low torque plug valve of the second transducer subassembly, a vibrator hose, a stand pipe, a top drive and a case running tool (CRT).

In an embodiment, a method of removing and replacing a drilling mud screen comprises a) providing the drilling mud screen system; b) stopping a drilling mud pump connected to the drilling mud screen system; c) opening a drilling mud screen access port in the drilling mud screen system to remove and replace a drilling mud screen; d) accessing the interior of the drilling mud screen system to pull the plug from the drilling mud screen system; e) accessing the interior of the drilling mud screen system to pull the drilling mud screen from the drilling mud screen system and to install a replacement drilling mud screen into the drilling mud screen system; f) accessing the interior of the drilling mud screen system to reinstall the plug into the drilling mud screen system; g) closing the drilling mud screen access port in the drilling mud screen system; and h) operating the drilling mud pump to produce flow of drilling mud through the drilling mud screen system.

In an embodiment, step d) comprises using a puller/installer plate and/or a rounded end of a puller/installer tool to engage and pull the plug from the drilling mud screen system. In an embodiment, step d) comprises using a puller/installer plate and/or a rounded end of a puller/installer tool to engage and pull the plug from the drilling mud screen system and, optionally using a stop plate, groove or painted line of the puller/installer tool to determine when the replacement drilling mud screen is installed into the drilling mud screen system.

In an embodiment, step e) comprises using a puller/installer plate of a puller/installer tool to engage and pull the drilling mud screen from the drilling mud screen system. In an embodiment, step e) comprises using a puller/installer plate and/or a rounded end of a puller/installer tool to install the replacement drilling mud screen into the drilling mud screen system.

In an embodiment, step f) comprises using a puller/installer plate and/or a rounded end of a puller/installer tool to reinstall the plug into the drilling mud screen system.

In an embodiment, a piston-style drilling mud screen system comprises an optional first assembly having a first drilling mud inlet, an optional second assembly having a fourth drilling mud outlet, a first body, a second body, a lock system and, optionally, a skid.

In an embodiment, a piston-style drilling mud screen system comprises a first assembly having a first drilling mud

inlet, a second assembly having a fourth drilling mud outlet, a first body, a second body, a lock system and, optionally, a skid.

In an embodiment, the first assembly has a first end and a second end, the first drilling mud inlet at the first end of the first assembly, and the first drilling mud outlet at the second end of the first assembly.

In an embodiment, the first body has a first end and a second end, a second drilling mud inlet at the first end of the first body, and a second drilling mud outlet at the second end of the first body. In an embodiment, the first drilling mud outlet of the first assembly is fluidly connected to the second drilling mud inlet of the first body. In an embodiment, the first drilling mud outlet of the first assembly is fluidly connected to the second drilling mud inlet of the first body via a quarter-turn breech lock connection.

In an embodiment, the first body has a first sleeve extending from the second end of the first body, and the second drilling mud outlet of the first body is fluidly connected to the third drilling mud inlet of the first body via the first sleeve. In an embodiment, the first sleeve is integral to the second end of the first body. In an embodiment, the first sleeve is fluidly connected to the second end of the first body.

In an embodiment, the first end of the first body has a means to engage a drilling mud screen puller/installer tool.

In an embodiment, the second body has a first end and a second end, a third drilling mud inlet at the first end of the second body, and a third drilling mud outlet at the second end of the second body. In an embodiment, the second drilling mud outlet of the first body is fluidly connected to the third drilling mud inlet of the second body.

In an embodiment, the second body has a second sleeve extending from the first end of the second body, and the second drilling mud outlet of the first body is fluidly connected to the third drilling mud inlet of the second body via the second sleeve. In an embodiment, the second sleeve is integral to the first end of the second body. In an embodiment, the second sleeve is fluidly connected to the first end of the second body.

In an embodiment, a drilling mud screen is disposed within the first body and the second body between the first drilling mud inlet and the second drilling mud outlet.

In an embodiment, the lock system comprises a third body, a fourth body, a first lock and a second lock.

In an embodiment, the third body having a first end and a second end, a first inlet at the first end of the third body, and a first outlet at the second end of the third body. In an embodiment, the second end of the first body is disposed through the first end of the third body such that the second end of the first body is held by a lip at the first end of the third body.

In an embodiment, the third body of the lock system are capable of receiving a portion of the first body when the first lock is unlocked.

In an embodiment, the fourth body has a first end and a second end, a second inlet at the first end of the fourth body, and a second outlet at the second end of the fourth body. In an embodiment, the first outlet of the third body is connected to the second inlet of the fourth body. In an embodiment, the first outlet of the third body is connected to the second inlet of the fourth body via a threaded connection.

In an embodiment, the fourth body of the lock system is capable of receiving a portion of the second body when the second lock is unlocked.

In an embodiment, the first lock extends through the third body and engages the first body when the piston-style

drilling mud screen system is closed. In an embodiment, the first lock is a spring-loaded lock.

In an embodiment, the first end of the second body is disposed through the second end of the fourth body such that the first end of the second body is held by a lip at or near the second end of the fourth body.

In an embodiment, the second lock extends through the fourth body and engages the second body when the piston-style drilling mud screen system is closed. In an embodiment, the second lock is a spring-loaded lock.

In an embodiment, the second assembly has a first end and a second end, a fourth drilling mud inlet at the first end of the second assembly, and a fourth drilling mud outlet at the second end of the second assembly.

In an embodiment, the third drilling mud outlet of the second body is fluidly connected to the fourth drilling mud inlet of the second assembly.

In an embodiment, the third drilling mud outlet of the second body is fluidly connected to the fourth drilling mud inlet of the second assembly via a quarter-turn breech lock connection.

In an embodiment, the skid comprises a base, a first support, a second support and a third support.

In an embodiment, the first support has a first end and a second end, wherein the first end of the first support is attached to the base and wherein the second end of the first support is attached to the first assembly.

In an embodiment, the second support has a first end and a second end, wherein the first end of the second support is attached to the base and wherein the second end of the second support is attached to the second assembly.

In an embodiment, the third support has a first end and a second end, wherein the first end of the third support is attached to the base and wherein the second end of the third support is attached to the lock system.

In an embodiment, one or more of the first support, the second support and the third support is capable of being lowered, pivoted, raised, rotated or any combination thereof. In an embodiment, one or more of the first support, the second support and the third support is capable of being lowered, pivoted, raised, rotated or any combination thereof via a connection, coupling and/or extension. In an embodiment, the one or more of the first support, the second support and the third support is capable of being automatically lowered, pivoted, raised and/or rotated. In an embodiment, the one or more of the first support, the second support and the third support is capable of being manually lowered, pivoted, raised and/or rotated.

In an embodiment, the piston-style drilling mud screen system further comprises a transducer subassembly. In an embodiment, the transducer subassembly comprises a body having a drilling mud inlet, a drilling mud outlet and a transducer access port, and a transducer.

In an embodiment, the body has a first end, a second end and a first centerline from the first end to the second end.

In an embodiment, the drilling mud inlet is at the first end of the body.

In an embodiment, the first drilling mud outlet is at the second end of the first body.

In an embodiment, the transducer access port has a second centerline forming a transducer angle with the first centerline and extending to the first centerline, wherein the transducer access port is offset from the first end of the body. In an embodiment, the transducer angle is from about 20-degrees to about 120-degrees.

In an embodiment, the transducer is disposed within the transducer access port to close and seal the transducer access port.

In an embodiment, the drilling mud outlet of the transducer assembly is fluidly connected to the first drilling mud inlet of the piston-style drilling mud screen system. In an embodiment, the drilling mud outlet of the transducer subassembly is fluidly connected to the first drilling mud inlet of the piston-style drilling mud screen system via a cross-over connection.

In an embodiment, one or more of the first assembly, the second assembly, the first body, the second body, the third body and the fourth body are constructed from AISI 4130/75k or equivalent material, AISI 4145 or equivalent, or combinations thereof.

In an embodiment, the drilling mud screen is constructed from AISI 4145 or equivalent, stainless steel or combinations thereof. In an embodiment, the drilling mud screen has a hardened coating.

In an embodiment, a method of installing a piston-style drilling mud screen system comprises the steps of: a) providing the piston-style drilling mud screen system; b) stopping a drilling mud pump to fluidly connect the piston-style drilling mud screen to the drilling mud pump; c) fluidly connecting the piston-style drilling mud screen system in line with and immediately upstream or downstream of the drilling mud pump; and d) operating the drilling mud pump to produce flow of drilling mud through the piston-style drilling mud screen system.

In an embodiment, step c) comprises fluidly connecting a drilling mud inlet of the piston-style drilling mud screen system to a high-pressure outlet of the drilling mud pump and fluidly connecting a drilling mud outlet of the piston-style drilling mud screen system to a vibrator hose or a standpipe.

In an embodiment, step c) comprises fluidly connecting a drilling mud inlet of the piston-style drilling mud screen system to a high-pressure inlet of the drilling mud pump and fluidly connecting a drilling mud outlet of the piston-style drilling mud screen system to an inlet of a vibrator hose.

In an embodiment, step c) comprises fluidly connecting a drilling mud inlet of the piston-style drilling mud screen system to an outlet of a vibrator hose and a drilling mud outlet of the piston-style drilling mud screen system to an inlet of a standpipe.

In an embodiment, step c) comprises fluidly connecting a drilling mud inlet of the piston-style drilling mud screen system to an outlet of a first portion of a standpipe and a drilling mud outlet of the piston-style drilling mud screen system to an inlet of a second portion of the standpipe.

In an embodiment, the method further comprises step e) filtering or screening debris from drilling mud.

In an embodiment, a method of removing and replacing a drilling mud screen in a piston-style drilling mud screen system comprises the steps: a) providing a piston-style drilling mud screen system; b) stopping a drilling mud pump connected to the piston-style drilling mud screen system; c) opening the lock system in the piston-style drilling mud screen system to remove and replace a drilling mud screen; d) accessing the interior of the piston-style drilling mud screen system to pull the drilling mud screen from the piston-style drilling mud screen system and to install a replacement drilling mud screen into the piston-style drilling mud screen system; e) closing the lock system in the piston-style drilling mud screen system; and f) operating the drilling mud pump to produce flow of drilling mud through the piston-style drilling mud screen system.

11

In an embodiment, the method further comprises step (g) monitoring the transducer of the first transducer subassembly for property information immediately upstream of the piston-style drilling mud screen system and step (h) using the property information to determine a status of the piston-style drilling mud screen system.

In an embodiment, step c) comprises: (c-1) disengaging the first lock of the lock system from the first body and disengaging the second lock of the lock system from the second body of the piston-style drilling mud screen system; (c-2) rotating the first body to unlatch the first assembly and rotating the second body to unlatch the second assembly; and (c-3) sliding the first body further into the lock system to disengage the first assembly and sliding the second body into the lock system to disengage the second assembly.

In an embodiment, step c) further comprises: (c-4) lifting, lowering, pivoting, rotating, sliding or otherwise moving one or more of the first assembly, the second assembly, the lock system and any combination thereof to open the piston-style drilling mud screen system to remove the drilling mud screen.

In an embodiment, step d) further comprises using a puller/installer plate of a puller/installer tool to engage and pull the drilling mud screen from the drilling mud screen system.

In an embodiment, step d) further comprises using a puller/installer plate and/or a rounded end of a puller/installer tool to install the replacement drilling mud screen into the drilling mud screen system and, optionally, using a stop plate, groove or painted line of the puller/installer tool to determine when the replacement drilling mud screen is installed into the drilling mud screen system.

In an embodiment, step e) comprises: (e-1) lifting, lowering, pivoting, rotating, sliding or otherwise moving one or more of the first assembly, the second assembly, the lock system and any combination thereof to close the piston-style drilling mud screen system; (e-2) rotating the first body to latch the first assembly and rotating the second body to latch the second assembly; and (e-3) engaging the first lock of the lock system from the first body and engaging the second lock of the lock system from the second body of the piston-style drilling mud screen system.

In an embodiment, a method of installing a piston-style drilling mud screen system comprises the steps of: a) providing a piston-style drilling mud screen system; b) stopping a drilling mud pump; c) fluidly connecting a first transducer subassembly, having a transducer, in line with and downstream of the drilling mud pump and fluidly connecting the piston-style drilling mud screen system in line with and immediately downstream of the first transducer subassembly; and d) operating the drilling mud pump to produce flow of drilling mud through the first transducer subassembly and the piston-style drilling mud screen system.

In an embodiment, step (c) comprises fluidly connecting a first transducer subassembly, having a transducer, in line with and downstream of the drilling mud pump and fluidly connecting the piston-style drilling mud screen system in line with and immediately downstream of the first transducer subassembly, and fluidly connecting a gate valve in line with and immediately downstream of the piston-style drilling mud screen system, fluidly connecting a second transducer assembly, having a low torque plug valve, in line with and immediately downstream of the gate valve.

In an embodiment, step (d) comprises operating the drilling mud pump to produce flow of drilling mud through

12

the first transducer subassembly, the piston-style drilling mud screen system, the gate valve and the second transducer subassembly.

In an embodiment, the method further comprises step (e) stopping the drilling mud pump, step (f) closing the gate valve to isolate the piston-style drilling mud screen system, and step (g) pumping cement through the low torque plug valve of the second transducer subassembly, a vibrator hose, a stand pipe, a top drive and a case running tool (CRT).

10 In an embodiment, an alternate piston-style drilling mud screen system comprises an optional first assembly having a first drilling mud inlet, an optional second assembly having a fourth drilling mud outlet, a first body, a second body, a union system and, optionally, a skid.

15 In an embodiment, a piston-style drilling mud screen system comprises a first assembly having a first drilling mud inlet, a second assembly having a fourth drilling mud outlet, a first body, a second body, a union system and, optionally, a skid.

20 In an embodiment, the first assembly has a first end and a second end, the first drilling mud inlet at the first end of the first assembly, and the first drilling mud outlet at the second end of the first assembly.

In an embodiment, the first body has a first end and a 25 second end, a second drilling mud inlet at the first end of the first body, and a second drilling mud outlet at the second end of the first body. In an embodiment, the first drilling mud outlet of the first assembly is fluidly connected to the second drilling mud inlet of the first body. In an embodiment, the first drilling mud outlet of the first assembly is fluidly connected to the second drilling mud inlet of the first body via a connection.

30 In an embodiment, the second end of the first body is modified to reduce an inside surface exit angle to transition from a first inner diameter of the first body to a second inner diameter of the fifth body. In an embodiment, the exit angle is from about 10-degrees to about 90-degrees. In an embodiment, the exit angle is about 40-degrees.

In an embodiment, the first end of the first body has a 35 means to engage a drilling mud screen puller/installer tool.

In an embodiment, the second body has a first end and a second end, a third drilling mud inlet at the first end of the second body, and a third drilling mud outlet at the second end of the second body. In an embodiment, the second drilling mud outlet of the first body is fluidly connected to the third drilling mud inlet of the second body.

In an embodiment, the first end of the second body is modified to reduce an inside surface entry angle to transition from the second inner diameter of the fifth body to a third inner diameter of the second body. In an embodiment, the entry angle is from about 10-degrees to about 90-degrees. In an embodiment, the entry angle is about 30-degrees.

In an embodiment, a drilling mud screen is disposed within the first body and the second body between the first 45 drilling mud inlet and the second drilling mud outlet.

In an embodiment, the union system comprises a third body, a fourth body and a fifth body.

In an embodiment, the third body has a first inlet at a first end and a first outlet at second end.

50 In an embodiment, the fourth body has a second inlet at a first end and a second outlet at a second end.

In an embodiment, the fifth body has a first and second end. In an embodiment, the second end of the first body is disposed through the first end of the fifth body such that a 55 portion of the third body is disposed between the second end of the second body and a portion of the first end of the fifth body. In an embodiment, the first end of the second body is

13

disposed through the second end of the fifth body such that a portion of the fourth body is disposed between the first end of the second body and a portion of the second end of the fifth body.

In an embodiment, the second end of the third body and the first end of the fifth body form a first union; and the second end of the fifth body and the first end of the fourth body form a second union.

In an embodiment, the first drilling mud outlet of the first assembly is fluidly connected to the second drilling mud inlet of the first body via a connection.

In an embodiment, the third drilling mud outlet of the second body is fluidly connected to the fourth drilling mud inlet of the second assembly via a connection.

In an embodiment, the fifth body is capable of receiving a portion of the first body when the first drilling mud outlet of the first subassembly is opened.

In an embodiment, the fifth body is capable of receiving a portion of the second body when the second drilling mud inlet of the second subassembly is opened.

In an embodiment, the skid comprises a base, a first support, a second support and a third support.

In an embodiment, the first support has a first end and a second end, wherein the first end of the first support is attached to the base and wherein the second end of the first support is attached to the first assembly.

In an embodiment, the second support has a first end and a second end, wherein the first end of the second support is attached to the base and wherein the second end of the second support is attached to the second assembly.

In an embodiment, the third support has a first end and a second end, wherein the first end of the third support is attached to the base and wherein the second end of the third support is attached to the union system.

In an embodiment, one or more of the first support, the second support and the third support is capable of being lowered, pivoted, raised, rotated or any combination thereof.

In an embodiment, one or more of the first support, the second support and the third support is capable of being lowered, pivoted, raised, rotated or any combination thereof via a connection, coupling and/or extension. In an embodiment, the one or more of the first support, the second support and the third support is capable of being automatically lowered, pivoted, raised and/or rotated. In an embodiment, the one or more of the first support, the second support and the third support is capable of being manually lowered, pivoted, raised and/or rotated.

In an embodiment, the piston-style drilling mud screen system further comprises a transducer subassembly. In an embodiment, the transducer subassembly comprises a body having a drilling mud inlet, a drilling mud outlet and a transducer access port, and a transducer.

In an embodiment, the body has a first end, a second end and a first centerline from the first end to the second end.

In an embodiment, the drilling mud inlet is at the first end of the body.

In an embodiment, the first drilling mud outlet is at the second end of the body.

In an embodiment, the transducer access port has a second centerline forming a transducer angle with the first centerline and extending to the first centerline, wherein the transducer access port is offset from the first end of the body. In an embodiment, the transducer angle is from about 20-degrees to about 120-degrees.

In an embodiment, the transducer is disposed within the transducer access port to close and seal the transducer access port.

14

In an embodiment, the drilling mud outlet of the transducer assembly is fluidly connected to the first drilling mud inlet of the piston-style drilling mud screen system. In an embodiment, the drilling mud outlet of the transducer subassembly is fluidly connected to the first drilling mud inlet of the piston-style drilling mud screen system via a cross-over connection.

In an embodiment, one or more of the first assembly, the second assembly, the first body, the second body, the third body and the fourth body are constructed from AISI 4130/75k or equivalent material, AISI 4145 or equivalent, or combinations thereof.

In an embodiment, the drilling mud screen is constructed from AISI 4145 or equivalent, stainless steel or combinations thereof. In an embodiment, the drilling mud screen has a hardened coating.

In an embodiment, a method of installing a piston-style drilling mud screen system comprising the steps of: (a) providing the piston-style drilling mud screen system; (b) stopping a drilling mud pump to fluidly connect the piston-style drilling mud screen to the drilling mud pump; (c) fluidly connecting the piston-style drilling mud screen system in line with and immediately upstream or downstream of the drilling mud pump; and (d) operating the drilling mud pump to produce flow of drilling mud through the piston-style drilling mud screen system.

In an embodiment, step c) comprises fluidly connecting a drilling mud inlet of the piston-style drilling mud screen system to a high-pressure outlet of the drilling mud pump and fluidly connecting a drilling mud outlet of the piston-style drilling mud screen system to a vibrator hose or a standpipe.

In an embodiment, step c) comprises fluidly connecting a drilling mud inlet of the piston-style drilling mud screen system to a high-pressure inlet of the drilling mud pump and fluidly connecting a drilling mud outlet of the piston-style drilling mud screen system to an inlet of a vibrator hose.

In an embodiment, step c) comprises fluidly connecting a drilling mud inlet of the piston-style drilling mud screen system to an outlet of a vibrator hose and a drilling mud outlet of the piston-style drilling mud screen system to an inlet of a standpipe.

In an embodiment, step c) comprises fluidly connecting a drilling mud inlet of the piston-style drilling mud screen system to an outlet of a first portion of a standpipe and a drilling mud outlet of the piston-style drilling mud screen system to an inlet of a second portion of the standpipe.

In an embodiment, the method further comprises step e) filtering or screening debris from drilling mud.

In an embodiment, a method of removing and replacing a drilling mud screen in a piston-style drilling mud screen system comprising the steps: (a) providing the piston-style drilling mud screen system; (b) stopping a drilling mud pump connected to the piston-style drilling mud screen system; (c) opening the first drilling mud outlet of the first subassembly and/or the second drilling mud inlet of the second subassembly in the piston-style drilling mud screen system to remove and replace a drilling mud screen; (d) accessing the interior of the piston-style drilling mud screen system to pull the drilling mud screen from the piston-style drilling mud screen system and to install a replacement drilling mud screen into the piston-style drilling mud screen system; (e) closing the first drilling mud outlet of the first subassembly and/or the second drilling mud inlet of the second subassembly in the piston-style drilling mud screen

15

system; and (f) operating the drilling mud pump to produce flow of drilling mud through the piston-style drilling mud screen system.

In an embodiment, step c) comprises: (c-1) rotating the first body to disengage the first assembly and/or rotating the second body to disengage the second assembly; and (c-2) sliding the first body further into the union system to fully disengage the first assembly and/or sliding the second body into the union system to fully disengage the second assembly. In an embodiment, step c) further comprises: (c-3) lifting, lowering, pivoting, rotating, sliding or otherwise moving one or more of the first assembly, the second assembly, the union system and any combination thereof to open the piston-style drilling mud screen system to remove the drilling mud screen.

In an embodiment, step d) further comprises using a puller/installer plate of a puller/installer tool to engage and pull the drilling mud screen from the drilling mud screen system. In an embodiment, step d) further comprises using a puller/installer plate and/or a rounded end of a puller/installer tool to install the replacement drilling mud screen into the drilling mud screen system and, optionally, using a stop plate, groove or painted line of the puller/installer tool to determine when the replacement drilling mud screen is installed into the drilling mud screen system.

In an embodiment, step e) comprises: (e-1) lifting, lowering, pivoting, rotating, sliding or otherwise moving one or more of a first assembly, a second assembly, the union system and any combination thereof to close the piston-style drilling mud screen system; (e-2) sliding the first body to engage the first assembly and/or sliding the second body to engage the second body; and (e-3) rotating the first body to fully engage the first assembly and/or rotating the second body to fully engage the second assembly.

In an embodiment, a method of installing a piston-style drilling mud screen system comprising the steps of: (a) providing the piston-style drilling mud screen system; (b) stopping a drilling mud pump; (c) fluidly connecting a first transducer subassembly, having a transducer, in line with and downstream of the drilling mud pump and fluidly connecting the piston-style drilling mud screen system in line with and immediately downstream of the first transducer subassembly; and (d) operating the drilling mud pump to produce flow of drilling mud through the first transducer subassembly and the piston-style drilling mud screen system.

In an embodiment, step (c) comprises fluidly connecting a first transducer subassembly, having a transducer, in line with and downstream of the drilling mud pump and fluidly connecting the piston-style drilling mud screen system in line with and immediately downstream of the first transducer subassembly, and fluidly connecting a gate valve in line with and immediately downstream of the piston-style drilling mud screen system, fluidly connecting a second transducer assembly, having a low torque plug valve, in line with and immediately downstream of the gate valve and wherein step (d) comprises operating the drilling mud pump to produce flow of drilling mud through the first transducer subassembly, the piston-style drilling mud screen system, the gate valve and the second transducer subassembly.

In an embodiment, the method further comprises step (e) monitoring the transducer of the first transducer subassembly for property information immediately upstream of the piston-style drilling mud screen system and step (f) using the property information to determine a status of the piston-style drilling mud screen system.

16

In an embodiment, the method further comprises step (e) stopping the drilling mud pump, step (f) closing the gate valve to isolate the piston-style drilling mud screen system, and step (g) pumping cement through the low torque plug valve of the second transducer subassembly, a vibrator hose, a stand pipe, a top drive and a case running tool (CRT).

In an embodiment, a flow loop configuration comprises a first drilling mud manifold or Y-connector, a drilling mud screen system and a second drilling mud manifold or T-connector.

In an embodiment, the flow loop configuration comprises a first drilling mud manifold having a first drilling mud inlet and a plurality of first drilling mud outlets; a plurality of drilling mud screen systems comprising: a first body having a first end, a second end and a first centerline from the first end to the second end; a first drilling mud inlet having a second centerline forming a first angle with the first centerline and extending to the first centerline, wherein the first drilling mud inlet is offset from the first end of the first body and wherein the first angle is from about 20-degrees to about 120-degrees; a first drilling mud outlet at the second end of the first body; a drilling mud screen access port at the first end of the first body; a first end cap, disposed within the drilling mud access port to close and seal the drilling mud access port; and a drilling mud screen, disposed within the first body between the first drilling mud inlet and the first drilling mud outlet; a second drilling mud manifold having a plurality of second drilling mud inlets and a second drilling mud outlet; wherein one of the plurality of first drilling mud outlets are fluidly connected to each of the first drilling mud inlets of the plurality of drilling mud screen systems; and wherein each the first drilling mud outlets of the plurality of drilling mud screen systems are fluidly connected to one of the plurality of second drilling mud inlets of the second drilling mud manifold.

In an embodiment, the first body comprises a second and a third body and wherein the second body is fluidly connected to the third body.

In an embodiment, the flow loop configuration further comprises a first plurality of gate valves, wherein each of the plurality of first drilling mud outlets of the first manifold are fluidly connected to one of the first plurality of gate valves and each of the first plurality of gate valves is fluidly connected to one of the first drilling mud inlets of the plurality of drilling mud screen systems.

In an embodiment, flow loop configuration further comprises a second plurality of gate valves, wherein each of the first drilling mud outlets of the plurality of drilling mud screen systems is fluidly connected to one of the second plurality of gate valves and each of the second plurality of gate valves is fluidly connected to one of second drilling mud inlets of the second manifold.

In an embodiment, the flow loop configuration further comprises a first gate valve, wherein the first gate valve is fluidly connected to the first drilling mud inlet of the first drilling mud manifold.

In an embodiment, the flow loop configuration further comprises a second gate valve, wherein the second gate valve is fluidly connected to the second drilling mud outlet of the second drilling mud manifold.

In an embodiment, a flow loop configuration comprises a first drilling mud manifold or Y-connector, a piston-style drilling mud screen system comprising a lock system or a union system and a second drilling mud manifold or T-connector.

In an embodiment, the flow loop configuration further comprises a first plurality of gate valves, wherein each of the

plurality of first drilling mud outlets of the first manifold are fluidly connected to one of the first plurality of gate valves and each of the first plurality of gate valves is fluidly connected to one of the first drilling mud inlets of the plurality of drilling mud screen systems.

In an embodiment, the flow loop configuration further comprises a second plurality of gate valves, wherein each of the first drilling mud outlets of the plurality of drilling mud screen systems is fluidly connected to one of the second plurality of gate valves and each of the second plurality of gate valves is fluidly connected to one of second drilling mud inlets of the second manifold.

In an embodiment, a drilling mud screen comprises a first body having a first end and a second end and a first centerline, a filter having a first end, a second end, and openings, wherein the second end of the filter is fluidly connected to the first end of the first body via a first connection and/or an optional first end retaining ring, a first end cap fluidly connected at the first end of the filter via a second connection, wherein the filter has an optional retaining ring disposed between the first connection and the second connection, a drilling mud inlet at the openings of the filter, and a drilling mud outlet at the second end of the first body.

In an embodiment, the first body and/or filter is constructed from alloy steel, tool steel, or combinations thereof. In an embodiment, the first body and/or filter is constructed from AISI 4130/75k or equivalent material, AISI 4145 or equivalent, or combinations thereof.

In an embodiment, the first body and/or filter has a hardened coating. In an embodiment, the first body and/or filter has a Carbide coating with about 6% Cobalt binder or equivalent.

In an embodiment, the filter comprises a plurality of rods having a first end and a second end. In an embodiment, the filter is tapered from the second end to the first end.

In an embodiment, the rods are spaced a distance apart to form the openings in the filter. In an embodiment, the rods are tapered from the first end to the second end.

In an embodiment, the filter comprises a formed sheet having drilled holes or slots spaced a distance apart to form the openings in the filter. In an embodiment, the filter is tapered from the second end to the first end.

In an embodiment, the drilled holes or slots are drilled in offset rows or straight rows from the first end to the second end.

In an embodiment, the first end cap is a flat plate or a flat plate with holes or slots.

In an embodiment, the first end cap is an inverted cone or an inverted cone with holes or slots.

In an embodiment, the first centerline of the first body and an outer surface of the first end cap forms a cap angle, wherein the cap angle is from about 30-degrees to about 90-degrees. In an embodiment, the first centerline of the first body and an outer surface of the first end cap forms a cap angle, wherein the cap angle is from about 35-degrees to about 45-degrees.

In an embodiment, the optional first end retaining ring and/or the optional retaining ring is/are modified to reduce inside surface entry and exit angles of the drilling mud screen.

In an embodiment, the entry and exit angles are from about 10 degrees to about 90-degrees. In an embodiment, the entry and exit angles are from about 10-degrees to about 50-degrees. In an embodiment, the entry and exit angles are about 30-degrees.

In an embodiment, the optional first end retaining ring and/or the optional retaining ring is constructed of alloy steel, stainless steel, or combinations thereof. In an embodiment, the optional first end retaining ring and/or the optional retaining ring is constructed from AISI 4145 or equivalent, stainless steel, or combinations thereof.

In an embodiment, the first end cap is constructed of alloy steel, stainless steel, or combinations thereof.

In an embodiment, the first end cap has a hardened coating. In an embodiment, the first end cap has a Carbide coating with about 6% Cobalt binder or equivalent material.

In an embodiment, the filter has a first section, a second section and a third section. In an embodiment, the first section is about 20-25% longer than the second section and/or the third section.

In an embodiment, an alternative drilling mud screen system comprises a second body having a first drilling mud inlet, a first drilling mud outlet and a drilling mud screen access port, a reversed drilling mud screen as discussed herein, and a second end cap. In an embodiment, the first drilling mud outlet is adapted to be fluidly connected to an inlet of a vibrator hose or an inlet to a standpipe or at any point in the standpipe.

In an embodiment, the second body has a first end, a second end and a second centerline from the first end to the second end.

In an embodiment, the first drilling mud inlet has a third centerline forming a first angle with the second centerline and extending to the second centerline, wherein the first drilling mud inlet is offset from the first end of the second body. In an embodiment, the first angle is from about 20-degrees to about 120-degrees.

In an embodiment, the first drilling mud outlet is at the second end of the second body.

In an embodiment, the drilling mud screen access port is at the first end of the second body. In an embodiment, the second end cap is disposed within the drilling mud access port to close and seal the drilling mud access port.

In an embodiment, the reversed drilling mud screen is disposed within the second body between the first drilling mud inlet and the first drilling mud outlet.

In an embodiment, the reversed drilling mud screen is constructed from AISI 4145 or equivalent, stainless steel or combinations thereof. In an embodiment, the reversed drilling mud screen has a hardened coating.

In an embodiment, the second body comprises a third body and a fourth body, and wherein the third body is fluidly connected to the fourth body via a union.

In an embodiment, the first body has a first portion and a second portion surrounding the filter. In an embodiment, a first inner diameter of the first portion is larger than a second inner diameter of the second portion to provide a high flow rate of drilling mud through the filter.

In an embodiment, one or more of the first body, the second body, the third body and the fourth body are constructed from AISI 4130/75k or equivalent material, AISI 4145 or equivalent, or combinations thereof.

In an embodiment, the filter comprises a plurality of rods having a first end and a second end. In an embodiment, the filter is tapered from the second end to the first end.

In an embodiment, the rods are spaced a distance apart to form the openings in the filter. In an embodiment, the rods are tapered from the first end to the second end.

In an embodiment, the filter comprises a formed sheet having drilled holes or slots spaced a distance apart to form the openings in the filter. In an embodiment, the filter is tapered from the second end to the first end.

In an embodiment, the drilled holes or slots are drilled in offset rows or straight rows from the first end to the second end.

In an embodiment, the first end cap is a flat plate or a flat plate with holes or slots.

In an embodiment, the first end cap is an inverted cone or an inverted cone with holes or slots.

In an embodiment, the first centerline of the first body and an outer surface of the first end cap forms a cap angle, wherein the cap angle is from about 30-degrees to about 90-degrees. In an embodiment, the first centerline of the first body and an outer surface of the first end cap forms a cap angle, wherein the cap angle is from about 35-degrees to about 45-degrees.

In an embodiment, the filter, the first end retaining ring and/or the retaining ring are constructed from AISI 4145 or equivalent, stainless steel or combinations thereof. In an embodiment, the filter, the first end retaining ring and/or the retaining ring has a hardened coating. In an embodiment, the filter, the first end retaining ring and/or the retaining ring has a Carbide coating with about 6% Cobalt binder.

In an embodiment, the drilling mud screen system further comprises a transducer subassembly. In an embodiment, the transducer subassembly comprises a transducer body having a drilling mud inlet, a drilling mud outlet and a transducer access port, and a transducer.

In an embodiment, the transducer body has a first end, a second end and a third centerline from the first end to the second end.

In an embodiment, the drilling mud inlet is at the first end of the transducer body.

In an embodiment, the first drilling mud outlet is at the second end of the transducer body.

In an embodiment, the transducer access port has a fourth centerline forming a transducer angle with the third centerline and extending to the third centerline, wherein the transducer access port is offset from the first end of the transducer body. In an embodiment, the transducer angle is from about 20-degrees to about 120-degrees.

In an embodiment, the transducer is disposed within the transducer access port to close and seal the transducer access port.

In an embodiment, the drilling mud outlet of the transducer assembly is fluidly connected to the first drilling mud inlet of the drilling mud screen system.

In an embodiment, a method of installing a drilling mud screen comprise (a) stopping a drilling mud pump to fluidly connect a drilling mud screen as discussed herein to the drilling mud pump, (b) fluidly connecting the drilling mud screen system in line with and immediately upstream or downstream of the drilling mud pump, and (c) operating the drilling mud pump to produce flow of drilling mud through the drilling mud screen system.

In an embodiment, step b) comprises fluidly connecting a drilling mud inlet of the drilling mud screen to a high-pressure outlet of the drilling mud pump and fluidly connecting a drilling mud outlet of the drilling mud screen to a vibrator hose or a standpipe. In an embodiment, step b) comprises fluidly connecting a drilling mud inlet of the drilling mud screen to a high-pressure inlet of the drilling mud pump and fluidly connecting a drilling mud outlet of the drilling mud screen to an inlet of a vibrator hose. In an embodiment, step b) comprises fluidly connecting a drilling mud inlet of the drilling mud screen to an outlet of a vibrator hose and a drilling mud outlet of the drilling mud screen to an inlet of a standpipe. In an embodiment, step b) comprises fluidly connecting a drilling mud inlet of the drilling mud

screen to an outlet of a first portion of a standpipe and a drilling mud outlet of the drilling mud screen to an inlet of a second portion of the standpipe.

In an embodiment, the method further comprises step d) filtering or screening debris from drilling mud.

In an embodiment, a method of installing a drilling mud screen system comprises (a) stopping a drilling mud pump to fluidly connect a drilling mud screen as discussed herein to the drilling mud pump, (b) fluidly connecting the drilling mud screen system in line with and immediately upstream or downstream of the drilling mud pump, and (c) operating the drilling mud pump to produce flow of drilling mud through the drilling mud screen system.

In an embodiment, step b) comprises fluidly connecting a drilling mud inlet of the drilling mud screen system to a high-pressure outlet of the drilling mud pump and fluidly connecting a drilling mud outlet of the drilling mud screen system to a vibrator hose or a standpipe. In an embodiment, step b) comprises fluidly connecting a drilling mud inlet of the drilling mud screen system to a high-pressure inlet of the drilling mud pump and fluidly connecting a drilling mud outlet of the drilling mud screen system to an inlet of a vibrator hose. In an embodiment, step b) comprises fluidly connecting a drilling mud inlet of the drilling mud screen system to an outlet of a vibrator hose and a drilling mud outlet to an inlet of a standpipe. In an embodiment, step b) comprises fluidly connecting a drilling mud inlet of the drilling mud screen system to an outlet of a first portion of a standpipe and a drilling mud outlet of the drilling mud screen system to an inlet of a second portion of the standpipe.

In an embodiment, the method further comprises step d) filtering or screening debris from drilling mud.

In an embodiment, a method of removing and replacing a drilling mud screen comprises (a) stopping a drilling mud pump connected to a drilling mud screen system as discussed herein, (b) opening a drilling mud screen access port and/or a union in the drilling mud screen system to remove and replace the drilling mud screen, (c) accessing the interior of the drilling mud screen system to pull the drilling mud screen from the drilling mud screen system and to install a replacement drilling mud screen into the drilling mud screen system, (d) closing the drilling mud screen access port and/or the union in the drilling mud screen system, and (e) operating the drilling mud pump to produce flow of drilling mud through the drilling mud screen system.

In an embodiment, step b) comprises opening a drilling mud screen access port in the body of the drilling mud screen system. In an embodiment, step b) comprises opening the drilling mud screen access port of the third body and opening a union between the third body and the fourth body of the drilling mud screen system to remove and replace the drilling mud screen.

In an embodiment, step d) comprises closing the drilling mud screen access port in the body of the drilling mud screen system. In an embodiment, step d) comprises closing the drilling mud screen access port of the third body and connecting the union between the third body and the fourth body of the drilling mud screen system.

In an embodiment, a method of installing a drilling mud screen system comprises (a) stopping a drilling mud pump, (b) fluidly connecting a first transducer subassembly, having a first transducer, in line with and downstream of the drilling mud pump and fluidly connecting a drilling mud screen system as discussed herein in line with and immediately downstream of the first transducer subassembly, and (c)

21

operating the drilling mud pump to produce flow of drilling mud through the first transducer subassembly and the drilling mud screen system.

In an embodiment, the method further comprises step (d) monitoring the first transducer of the first transducer subassembly for property information immediately upstream of the drilling mud screen system, and step (e) using the property information to determine a status of the drilling mud screen system.

In an embodiment, step (b) comprises (b-1) fluidly connecting the first transducer subassembly, having the first transducer, in line with and downstream of the drilling mud pump, (b-2) fluidly connecting the drilling mud screen system in line with and immediately downstream of the first transducer subassembly, (b-3) fluidly connecting a gate valve in line with and immediately downstream of the drilling mud screen system, and (b-4) fluidly connecting a second transducer assembly, having a low torque plug valve, in line with and immediately downstream of the gate valve.

In an embodiment, step (c) comprises operating the drilling mud pump to produce flow of drilling mud through the first transducer subassembly, the drilling mud screen system, the gate valve and the second transducer subassembly.

In an embodiment, the method further comprises step (d) stopping the drilling mud pump, step (e) closing the gate valve to isolate the drilling mud screen system, and step (f) pumping cement through the low torque plug valve of the second transducer subassembly, a vibrator hose, a stand pipe, a top drive and a case running tool (CRT).

In an embodiment, a second alternate piston-style drilling mud screen system comprises an optional first assembly having a first drilling mud inlet, an optional second assembly having a fourth drilling mud outlet, a reversed drilling mud screen, a second body, a third body, a union system and, optionally, a skid.

In an embodiment, a piston-style drilling mud screen system comprises a first assembly having a first drilling mud inlet, a second assembly having a fourth drilling mud outlet, a reversed drilling mud screen as discussed herein, a second body, a third body, a union system and, optionally, a skid.

In an embodiment, the first assembly has a first end and a second end, the first drilling mud inlet at the first end of the first assembly, and the first drilling mud outlet at the second end of the first assembly.

In an embodiment, the second body has a first end and a second end, a second drilling mud inlet at the first end of the second body, and a second drilling mud outlet at the second end of the second body. In an embodiment, the first drilling mud outlet of the first assembly is fluidly connected to the second drilling mud inlet of the second body. In an embodiment, the first drilling mud outlet of the first assembly is fluidly connected to the second drilling mud inlet of the second body via a connection.

In an embodiment, the second end of the second body is modified to reduce an inside surface exit angle to transition from a first inner diameter of the second body to a second inner diameter of the sixth body. In an embodiment, the exit angle is from about 10-degrees to about 90-degrees. In an embodiment, the exit angle is about 40-degrees.

In an embodiment, the third body has a first end and a second end, a third drilling mud inlet at the first end of the third body, and a third drilling mud outlet at the second end of the third body. In an embodiment, the second drilling mud outlet of the second body is fluidly connected to the third drilling mud inlet of the third body.

In an embodiment, the first end of the third body is modified to reduce an inside surface entry angle to transition

22

from the second inner diameter of the sixth body to a third inner diameter of the third body. In an embodiment, the entry angle is from about 10-degrees to about 90-degrees. In an embodiment, the entry angle is about 30-degrees.

5 In an embodiment, the reversed drilling mud screen is disposed within the second body and the third body between the first drilling mud inlet and the second drilling mud outlet.

In an embodiment, the union system comprises a fourth body, a fifth body and a sixth body.

10 In an embodiment, the fourth body has a first inlet at a first end and a first outlet at second end.

In an embodiment, the fifth body has a second inlet at a first end and a second outlet at a second end.

In an embodiment, the sixth body has a first and second 15 end. In an embodiment, the second end of the second body is disposed through the first end of the sixth body such that a portion of the fourth body is disposed between the second end of the third body and a portion of the first end of the sixth body. In an embodiment, the first end of the third body is disposed through the second end of the sixth body such that a portion of the fifth body is disposed between the first end of the third body and a portion of the second end of the sixth body.

20 In an embodiment, the second end of the fourth body and the first end of the sixth body form a first union; and the second end of the sixth body and the first end of the fifth body form a second union.

In an embodiment, the first drilling mud outlet of the first 25 assembly is fluidly connected to the second drilling mud inlet of the first body via a connection.

In an embodiment, the third drilling mud outlet of the third body is fluidly connected to the fourth drilling mud inlet of the second assembly via a connection.

In an embodiment, the first drilling mud outlet of the first 30 assembly is fluidly connected to the second drilling mud inlet of the second body via a connection.

In an embodiment, the third drilling mud outlet of the third body is fluidly connected to the fourth drilling mud inlet of the second assembly via a connection.

35 In an embodiment, the first outlet of the fourth body is connected to the second inlet of the fifth body via a connection.

In an embodiment, the sixth body is capable of receiving a portion of the second body when the first drilling mud 40 outlet of the first subassembly is opened.

In an embodiment, the sixth body is capable of receiving a portion of the third body when the second drilling mud inlet of the second subassembly is opened.

In an embodiment, the skid comprises a base, a first 45 support, a second support and a third support.

In an embodiment, the first support has a first end and a second end, wherein the first end of the first support is attached to the base and wherein the second end of the first support is attached to the first assembly.

50 In an embodiment, the second support has a first end and a second end, wherein the first end of the second support is attached to the base and wherein the second end of the second support is attached to the second assembly.

In an embodiment, the third support has a first end and a second end, wherein the first end of the third support is attached to the base and wherein the second end of the third support is attached to the union system.

55 In an embodiment, one or more of the first support, the second support and the third support is capable of being lowered, pivoted, raised, rotated or any combination thereof.

In an embodiment, one or more of the first support, the second support and the third support is capable of being

lowered, pivoted, raised, rotated or any combination thereof via a connection, coupling and/or extension. In an embodiment, the one or more of the first support, the second support and the third support is capable of being automatically lowered, pivoted, raised and/or rotated. In an embodiment, the one or more of the first support, the second support and the third support is capable of being manually lowered, pivoted, raised and/or rotated.

In an embodiment, the piston-style drilling mud screen system further comprises a transducer subassembly. In an embodiment, the transducer subassembly comprises a transducer body having a drilling mud inlet, a drilling mud outlet and a transducer access port, and a transducer.

In an embodiment, the transducer body has a first end, a second end and a first centerline from the first end to the second end.

In an embodiment, the drilling mud inlet is at the first end of the transducer body.

In an embodiment, the first drilling mud outlet is at the second end of the transducer body.

In an embodiment, the transducer access port has a second centerline forming a transducer angle with the first centerline and extending to the first centerline, wherein the transducer access port is offset from the first end of the transducer body. In an embodiment, the transducer angle is from about 20-degrees to about 120-degrees.

In an embodiment, the transducer is disposed within the transducer access port to close and seal the transducer access port.

In an embodiment, the drilling mud outlet of the transducer assembly is fluidly connected to the first drilling mud inlet of the piston-style drilling mud screen system. In an embodiment, the drilling mud outlet of the transducer subassembly is fluidly connected to the first drilling mud inlet of the piston-style drilling mud screen system via a cross-over connection.

In an embodiment, one or more of the first assembly, the second assembly, the second body, the third body, the fourth body, the fifth body and the sixth body are constructed from AISI 4130/75k or equivalent material, AISI 4145 or equivalent, or combinations thereof.

In an embodiment, the reversed drilling mud screen is constructed from AISI 4145 or equivalent, stainless steel or combinations thereof.

In an embodiment, the reversed drilling mud screen has a hardened coating.

In an embodiment, a method of removing and replacing a drilling mud screen in a piston-style drilling mud screen system comprises (a) stopping a drilling mud pump connected to the piston-style drilling mud screen system as discussed herein, (b) opening the first drilling mud outlet of the first subassembly and/or the second drilling mud inlet of the second subassembly in the piston-style drilling mud screen system to remove and replace a drilling mud screen, (c) accessing the interior of the piston-style drilling mud screen system to pull the drilling mud screen from the piston-style drilling mud screen system and to install a replacement drilling mud screen into the piston-style drilling mud screen system, (d) closing the first drilling mud outlet of the first subassembly and/or the second drilling mud inlet of the second subassembly in the piston-style drilling mud screen system, and (e) operating the drilling mud pump to produce flow of drilling mud through the piston-style drilling mud screen system.

In an embodiment, step (b) comprises (b-1) rotating the second body to disengage the first assembly and/or rotating the third body to disengage the second assembly, and (b-2)

sliding the second body further into the union system to fully disengage the first assembly and/or sliding the third body into the union system to fully disengage the second assembly. In an embodiment, step (b) further comprises (b-3) lifting, lowering, pivoting, rotating, sliding or otherwise moving one or more of the first assembly, the second assembly, the union system and any combination thereof to open the piston-style drilling mud screen system to remove the drilling mud screen.

In an embodiment, step (d) comprises (d-1) lifting, lowering, pivoting, rotating, sliding or otherwise moving one or more of a first assembly, a second assembly, the union system and any combination thereof to close the piston-style drilling mud screen system, (d-2) sliding the second body to engage the first assembly and/or sliding the third body to engage the second body, and (d-3) rotating the second body to fully engage the first assembly and/or rotating the third body to fully engage the second assembly.

In an embodiment, a method of installing a piston-style drilling mud screen system comprises (a) stopping a drilling mud pump, (b) fluidly connecting a first transducer subassembly, having a first transducer, in line with and downstream of the drilling mud pump and fluidly connecting the piston-style drilling mud screen system as discussed herein in line with and immediately downstream of the first transducer subassembly, and (c) operating the drilling mud pump to produce flow of drilling mud through the first transducer subassembly and the piston-style drilling mud screen system.

In an embodiment, the method further comprises step (d) monitoring the transducer of the first transducer subassembly for property information immediately upstream of the piston-style drilling mud screen system and step (e) using the property information to determine a status of the piston-style drilling mud screen system.

In an embodiment, step (b) comprises (b-1) fluidly connecting the first transducer subassembly, having the first transducer, in line with and downstream of the drilling mud pump and fluidly connecting the piston-style drilling mud screen system as discussed herein in line with and immediately downstream of the first transducer subassembly, (b-2) fluidly connecting a gate valve in line with and immediately downstream of the piston-style drilling mud screen system, (b-3) fluidly connecting a second transducer assembly, having a low torque plug valve, in line with and immediately downstream of the gate valve.

In an embodiment, step (c) comprises operating the drilling mud pump to produce flow of drilling mud through the first transducer subassembly, the piston-style drilling mud screen system, the gate valve and the second transducer subassembly.

In an embodiment, the method further comprises step (d) stopping the drilling mud pump, step (e) closing the gate valve to isolate the piston-style drilling mud screen system, and step (f) pumping cement through the low torque plug valve of the second transducer subassembly, a vibrator hose, a stand pipe, a top drive and a case running tool (CRT).

These and other objects, features and advantages will become apparent as reference is made to the following detailed description, preferred embodiments, and examples, given for the purpose of disclosure, and taken in conjunction with the accompanying drawings and appended claims.

BRIEF DESCRIPTION OF THE DRAWINGS

The patent or application file contains at least one drawing executed in color. Copies of this patent or patent application

publication with color drawing(s) will be provided by the U.S. Patent and Trademark Office upon request and payment of a required fee.

For a further understanding of the nature and objects of the present invention, reference should be made to the following detailed disclosure, taken in conjunction with the accompanying drawings, in which like parts are given like reference numerals, and wherein:

FIG. 1 illustrates an image of an exemplary drilling mud screen system according to an embodiment of the present invention, showing the system installed at an outlet of a drilling mud pump upstream of a drilling rig standpipe assembly;

FIG. 2 illustrates an image of a single-piece body for the exemplary drilling mud screen system of FIG. 1, showing an unassembled view of a drilling mud inlet, a drilling mud outlet and a drilling mud screen access port;

FIG. 3A illustrates an image of a single-piece body for the exemplary drilling mud screen system of FIG. 2, showing a detailed view of a drilling mud inlet and a drilling mud screen access port;

FIG. 3B illustrates an image of a single-piece body for the exemplary drilling mud screen system of FIG. 3A, showing a detailed view of the drilling mud screen access port;

FIG. 3C illustrates an image of the single-piece body for the exemplary drilling mud screen system of FIG. 3A, showing an end cap installed in the drilling mud screen access port;

FIG. 3D illustrates an image of a single-piece body for the exemplary drilling mud screen system of FIGS. 3A-3C, showing a detailed view of the drilling mud inlet;

FIG. 3E illustrates an image of a single piece body of the exemplary drilling mud screen system of FIGS. 3A-3C, showing a detailed view of the drilling mud outlet;

FIG. 4A illustrates an upper, cross-sectional view of an exemplary drilling mud screen system according to an embodiment of the present invention, showing a drilling mud screen;

FIG. 4B illustrates a detailed view of A-A of FIG. 4A, showing an end cap installed;

FIG. 4C illustrates a detailed view of A-A of FIGS. 4A-4B, showing the end cap removed;

FIG. 5A illustrates an upper, cross-sectional view of a drilling mud screen according to an embodiment of the present invention, showing a filter and an end cap;

FIG. 5B illustrates a detailed view of A-A of FIG. 5A, showing an inlet of a second portion of a body and an outlet of the first portion of the body;

FIG. 5C illustrates a detailed view of B of FIG. 5A, showing a detailed view of a groove for an O-ring;

FIG. 5D illustrates a detailed view of C of FIG. 5A, showing an enlarged detailed view of the groove for an O-ring;

FIG. 5E illustrates an upper, right perspective view of the drilling mud screen of FIG. 5A;

FIG. 6A illustrates an image of a mud screen system according to an embodiment of the present invention, showing a two-piece body for the system;

FIG. 6B illustrates an image of the exemplary drilling mud screen system of FIG. 6A, showing a drilling mud outlet;

FIG. 6C illustrates an image of the exemplary drilling mud screen system of FIGS. 6A-6B;

FIG. 6D illustrates an image of the exemplary drilling mud screen system of FIGS. 6A-6C, showing a drilling mud inlet and a drilling mud screen access port;

FIG. 7A illustrates an upper, cross-sectional view of a drilling mud screen system according to an embodiment of the present invention, showing a single-inlet drilling mud system;

5 FIG. 7B illustrates an upper, cross-sectional view of a drilling mud screen system according to an embodiment of the present invention, showing a double-inlet drilling mud system;

10 FIG. 8A illustrates an upper cross-sectional view of an exemplary drilling mud screen puller/installer tool for the exemplary drilling mud screen system of FIGS. 4A-4C;

15 FIG. 8B illustrates a detailed view of A-A of FIG. 8A, showing a means to engage a drilling mud screen according to an embodiment of the present invention;

15 FIG. 9A illustrates an upper cross-sectional view of an exemplary drilling mud screen puller/installer tool for the exemplary drilling mud screen system of FIG. 7A;

20 FIG. 9B illustrates a detailed view of A-A of FIG. 9A, showing a means to engage a drilling mud screen according to an embodiment of the present invention;

25 FIG. 10 illustrates a flow diagram for a method of using a drilling mud screen system;

FIG. 11 illustrates a flow diagram for a method of using a drilling mud screen puller/installer;

25 FIG. 12A illustrates a cross-sectional view of the exemplary drilling mud tool of FIG. 8A pulling the drilling mud screen of FIG. 5 from the exemplary drilling mud screen system of FIG. 4;

30 FIG. 12B illustrates a cross-sectional view of the exemplary drilling mud tool of FIG. 8A installing the drilling mud screen of FIG. 5 into the exemplary drilling mud screen system of FIG. 4;

35 FIG. 13A illustrates a cross-sectional view of the exemplary drilling mud tool of FIG. 9A pulling the drilling mud screen of FIG. 5 from the exemplary drilling mud screen system of FIG. 7A;

FIG. 13B illustrates a cross-sectional view of the exemplary drilling mud tool of FIG. 9A installing the drilling mud screen of FIG. 5 into the exemplary drilling mud screen system of FIG. 7A;

40 FIG. 14 illustrates a cross-sectional view of the exemplary drilling mud screen of FIG. 4, showing an optional plug installed in the drilling mud screen system;

FIG. 15A illustrates an upper, right perspective view of an optional plug with a backward "J" shaped flow surface according to an embodiment of the present invention;

45 FIG. 15B illustrates a cross-sectional view of the optional plug with the backward "J" shaped flow surface of FIG. 15A;

50 FIG. 16A illustrates an upper, right perspective view of an optional plug with a curved shaped flow surface according to an embodiment of the present invention;

FIG. 16B illustrates a cross-sectional view of the optional plug with the curved shaped flow surface of FIG. 16A;

55 FIG. 17A illustrates an upper, right side perspective view of an optional plug with an "L" shaped flow surface according to an embodiment of the present invention;

60 FIG. 17B illustrates a cross-sectional view of an optional plug with an "L" shaped flow surface of FIG. 17A;

FIG. 18A illustrates an upper cross-sectional view of the exemplary drilling mud tool of FIG. 8A for the exemplary drilling mud system of FIGS. 4A-4C and 14;

65 FIG. 18B illustrates another upper cross-sectional view of the exemplary drilling mud tool of FIG. 8A for the exemplary drilling mud system of FIGS. 4A-4C and 14;

FIG. 19 illustrates a cross-sectional view of the drilling mud screen system in a monitoring configuration according

to an embodiment of the present invention, showing an optional transducer subassembly;

FIG. 20A illustrates an upper, right side perspective view of an optional transducer subassembly according to an embodiment of the present invention;

FIG. 20B illustrates a side perspective view of the optional transducer subassembly of FIG. 20A;

FIG. 21A illustrates an upper view of a mud screen system according to an embodiment of the present invention, showing an optional two-piece body for the system;

FIG. 21B illustrates a detailed, cross-sectional view of A-A of FIG. 21A, showing an entry angle of about 30 degrees;

FIG. 22A illustrates an end view of an optional drilling mud screen according to an embodiment of the present invention;

FIG. 22B illustrates a detailed, cross-sectional view of A-A of FIG. 22A, showing an optional drilling mud screen insert, and optional first end retaining ring, an optional filter length, and an optional filter retaining ring;

FIG. 22C illustrates a detailed view of B of FIG. 22B;

FIG. 22D illustrates a detailed, cross-sectional view of C-C of FIG. 22C;

FIG. 22E illustrates an upper, right perspective view of the drilling mud screen of FIGS. 22A-22B;

FIG. 23 illustrates a cross-sectional view of a mud screen system according to an embodiment of the present invention, showing an optional drilling mud screen insert inserted into a drilling mud screen;

FIG. 24A illustrates an end view of an optional drilling mud screen insert according to an embodiment of the present invention;

FIG. 24B illustrates a detailed, cross-sectional view of A-A of FIG. 24A, showing an inlet of the drilling mud screen insert and an outlet of the drilling mud screen insert;

FIG. 24C illustrates an upper, right perspective view of the optional drilling mud screen insert of FIGS. 24A-24B;

FIG. 25 illustrates a detailed, cross-sectional view of the optional drilling mud screen, showing an optional first end retaining ring;

FIG. 26A illustrates a side view of an optional drilling mud screen according to an embodiment of the present invention, showing an optional filter length, and an optional filter retaining ring;

FIG. 26B illustrates a detailed, cross-sectional view of the optional drilling mud screen of FIG. 26A, showing an optional drilling mud screen insert, an optional filter length, and an optional filter retaining ring;

FIG. 27A illustrates an end view of an optional filter retaining ring according to an embodiment of the present invention;

FIG. 27B illustrates a detailed, cross-sectional view of A-A of FIG. 27A;

FIG. 27C illustrates a detailed, cross-sectional view of B of FIG. 27B;

FIG. 28 illustrates a cross-sectional view of a drilling mud screen system in a cementing configuration according to an embodiment of the present invention, showing an optional first transducer subassembly having an optional transducer, a drilling mud screen system, an optional gate valve and an optional second transducer subassembly having an optional low torque plug valve;

FIG. 29 illustrates a cross-sectional view of the exemplary drilling mud tool of FIG. 9A inserting the drilling mud screen of FIG. 5 or 22 into the exemplary drilling mud screen system of FIG. 7A or 21B, showing an optional stop plate;

FIG. 30A-1 illustrates a cross-sectional view of an exemplary piston-style drilling mud screen system according to an embodiment of the present invention, showing the piston-style drilling mud screen system mounted on a skid;

FIG. 30A-2 illustrates a cross-sectional view of an exemplary piston-style drilling mud screen system according to an embodiment of the present invention, showing the piston-style drilling mud screen system mounted on a skid;

FIG. 30A-3 illustrates a cross-sectional view of an exemplary piston-style drilling mud screen system according to an embodiment of the present invention, showing the piston-style drilling mud screen system mounted on a skid;

FIG. 30A-4 illustrates a cross-sectional view of an exemplary piston-style drilling mud screen system according to an embodiment of the present invention, showing the piston-style drilling mud screen system mounted on a skid;

FIG. 30B illustrates an upper, left perspective view of the exemplary piston-style drilling mud screen system of FIG. 30A, showing the piston-style drilling mud screen system in a closed position;

FIG. 30C illustrates an upper, left perspective view of the exemplary piston-style drilling mud screen system of FIGS. 30A-30B, showing the piston-style drilling mud screen system in an unlatched position;

FIG. 30D illustrates an upper, left perspective view of the exemplary piston-style drilling mud screen system of FIGS. 30A and 30C, showing the piston-style drilling mud screen system in an unlatched and rotated position for removal of a drilling mud screen;

FIG. 30E illustrates an upper, left perspective view of the exemplary piston-style drilling mud screen system of FIGS. 30A and 30D, showing the piston-style drilling mud screen system in an unlatched and rotated position after removal of the drilling mud screen;

FIG. 30F illustrates a detailed view of an exemplary positive lock mechanism for the exemplary piston-style drilling mud screen system of FIGS. 30A-30E, showing a spring-loaded lock mechanism;

FIG. 30G illustrates a detailed view of an exemplary breech lock connection for the exemplary piston-style drilling mud screen system of FIGS. 30A-30F, showing a quarter-turn breech lock connection;

FIG. 31 illustrates a detailed view of an optional end subassembly for a piston-style drilling mud screen system according to an embodiment of the present invention, providing a cross-over connection from a first subassembly and/or a second subassembly to an optional transducer subassembly;

FIG. 32 illustrates a flow diagram for a method of installing and removing a drilling mud screen from the exemplary piston-style drilling mud screen system of FIGS. 30A-30G;

FIG. 33A illustrates a cross-sectional view of an exemplary piston-style drilling mud screen system according to an embodiment of the present invention, showing the piston-style drilling mud screen system;

FIG. 33B illustrates a cross-sectional view of an exemplary piston-style drilling mud screen system according to an embodiment of the present invention, showing the piston-style drilling mud screen system;

FIG. 33C illustrates a cross-sectional view of an exemplary piston-style drilling mud screen system according to an embodiment of the present invention, showing the piston-style drilling mud screen system;

FIG. 34A illustrates an upper, right perspective view of the exemplary piston-style drilling mud screen system of

FIGS. 33A-33C, showing the piston-style drilling mud screen system in a closed position;

FIG. 34B illustrates a lower, left perspective view of the exemplary piston-style drilling mud screen system of FIGS. 33A-33C, showing the piston-style drilling mud screen system in a closed position;

FIG. 35 a flow diagram for a method of installing and removing a drilling mud screen for the exemplary in-line piston-style drilling mud screen system of FIGS. 33A-34B;

FIG. 36 illustrates a cross-sectional view of a drilling mud screen system in a flow loop configuration according to an embodiment of the present invention, showing a pair of drilling mud screen systems;

FIG. 37 illustrates an upper, right perspective view of the flow loop configuration of FIG. 36;

FIG. 38 illustrates a cross-sectional view of a drilling mud screen system in a flow loop configuration, showing four piston-style drilling mud screen systems;

FIG. 39A illustrates an upper, left perspective view of a drilling mud screen system in a flow loop configuration, showing eight drilling mud screen systems;

FIG. 39B illustrates a left side view of the flow loop configuration of FIG. 39A, showing a drilling mud inlet;

FIG. 39C illustrates a right side view of the flow loop configuration of FIG. 39A, showing a drilling mud outlet;

FIG. 39D illustrates a back view of the flow loop configuration of FIG. 39A;

FIG. 40A illustrates an upper, right perspective view of a drilling mud screen system in a flow loop configuration;

FIG. 40B illustrates a left side view of the flow loop configuration of FIG. 40A, showing a drilling mud inlet;

FIG. 40C illustrates a right side view of the flow loop configuration of FIG. 40A, showing a drilling mud outlet;

FIG. 40D illustrates a top view of the flow loop configuration of FIG. 40A; and

FIG. 41A illustrates a cross-sectional view of an exemplary drilling mud screen system according to an embodiment of the invention, showing a reversed drilling mud screen;

FIG. 41B illustrates a detailed view of the reversed drilling mud screen of FIG. 41A;

FIG. 42A-1 illustrates a cross-sectional view of an exemplary piston-style drilling mud screen system according to an embodiment of the invention, showing a reversed drilling mud screen;

FIG. 42A-2 illustrates a cross-sectional view of an exemplary piston-style drilling mud screen system according to an embodiment of the invention, showing a reversed drilling mud screen and

FIG. 42B illustrates a detailed view of the reversed drilling mud screen of FIGS. 42A-1 and 42A-2.

DETAILED DESCRIPTION OF EMBODIMENTS OF THE INVENTION

The following detailed description of various embodiments of the present invention references the accompanying drawings, which illustrate specific embodiments in which the invention can be practiced. While the illustrative embodiments of the invention have been described with particularity, it will be understood that various other modifications will be apparent to and can be readily made by those skilled in the art without departing from the spirit and scope of the invention. Accordingly, it is not intended that the scope of the claims appended hereto be limited to the examples and descriptions set forth herein but rather that the claims be construed as encompassing all the features of

patentable novelty which reside in the present invention, including all features which would be treated as equivalents thereof by those skilled in the art to which the invention pertains. Therefore, the scope of the present invention is defined only by the appended claims, along with the full scope of equivalents to which such claims are entitled.

Exemplary Drilling Mud Screen System

FIG. 1 illustrates an image of an exemplary drilling mud screen system according to an embodiment of the present invention, showing the system installed at an outlet of a drilling mud pump upstream of a drilling rig standpipe assembly. As shown in FIG. 1, the drilling mud screen system 100 has a body 105 having a first end 110 and a second end 115, a drilling mud inlet 120 and a drilling mud outlet 125, and a drilling mud screen access port 130. In an embodiment, the drilling mud screen access port 130 may be closed with an end cap 135.

In an embodiment, a drilling mud inlet 120 of the drilling mud screen system 100 may be fluidly connected to a high-pressure outlet of a drilling mud pump via a connection. In an embodiment, a drilling mud outlet 125 of the drilling mud screen system 100 may be fluidly connected to an inlet of a vibrator hose to a standpipe via a connection.

Alternatively, the drilling mud screen system 100 may be installed between an outlet of the vibrator hose and an inlet of the standpipe, or at any point in the standpipe via a connection.

In an embodiment, the drilling mud inlet 120 may be fluidly connected to, for example, an outlet to a drilling mud pump via a connection; and the drilling mud outlet 125 may be fluidly connected to, for example, an inlet to a vibrator hose via a connection. Any suitable connection may be used for the drilling mud inlet and the drilling mud outlet. For example, suitable connections include, but are not limited to, pipe fittings and welds. Connections are well known in the art. In an embodiment, the drilling mud inlet 120 may be fluidly connected to, for example, an outlet to a drilling mud pump via a weld; and the drilling mud outlet 125 may be fluidly connected to, for example, an inlet to a vibrator hose via a weld.

Single-Piece Body

FIG. 2 illustrates an image of a single-piece body for the exemplary drilling mud screen system of FIG. 1, showing an unassembled view of a drilling mud inlet 220, a drilling mud outlet 225, and a drilling mud screen access port 230. As shown in FIG. 2, the drilling mud screen system 200 has a body 205 having a first end 210 and a second end 215, an inlet 220 and an outlet 225, and a mud screen access port 230.

In an embodiment, the drilling mud inlet 220 may be fluidly connected to, for example, an outlet of a drilling mud pump via a connection; and the drilling mud outlet 225 may be fluidly connected to, for example, an inlet of a vibrator hose via a connection. Any suitable connection may be used for the drilling mud inlet 220 and the drilling mud outlet 225. For example, suitable connections include, but are not limited to, pipe fittings and welds. Connections are well known in the art. In an embodiment, the drilling mud inlet 220 may be fluidly connected to, for example, an outlet of a drilling mud pump via a weld; and the drilling mud outlet 225 may be fluidly connected to, for example, an inlet of a vibrator hose via a weld.

FIG. 3A illustrates an image of a single-piece body for the exemplary drilling mud screen system of FIG. 2, showing a detailed view of a drilling mud inlet 320 and a drilling mud screen access port 330. As shown in FIG. 3A, the drilling

31

mud screen system 300 has a body 305 having a first end 310, an inlet 320, a drilling mud screen access port 330, and an end cap 335.

FIG. 3B illustrates an image of the single-piece body of FIG. 3A, showing a detailed view of the drilling mud screen access port 330. As shown in FIG. 3B, the drilling mud screen system 300 has a body 305 having a first end 310, an inlet 320, and a drilling mud screen access port 330.

FIG. 3C illustrates an image of the single-piece body of FIG. 3A, showing an end cap 335 installed in a drilling mud screen access port 330. As shown in FIG. 3C, the drilling mud screen access port 330 of the drilling mud screen system 300 may be closed with an end cap 335 via a fitting. Any suitable fitting may be used. For example, suitable fittings include, but are not limited to, pipe fittings. Fittings are well known in the art.

In an embodiment, the drilling mud screen access port 330 of the drilling mud screen system 300 may be sealed with an end cap 335 via an O-ring. Any suitable O-ring may be used. For example, suitable O-rings include, but are not limited to, 300 Series O-rings. O-rings are well known in the art.

In an embodiment, the end cap 335 of the drilling mud screen system 300 may comprise a cap, an O-ring and a pipe collar. In an embodiment, the end cap 335 may be a five-inch 1002 WECO cap with an O-ring.

FIG. 3D illustrates an image of a single-piece body of the exemplary drilling mud screen system of FIGS. 3A-3C, showing a detailed view of the drilling mud inlet 320; and FIG. 3E illustrates an image of a single-piece body of the exemplary drilling mud screen system of FIGS. 3A-3C, showing a detailed view of the drilling mud outlet 325.

In an embodiment, the drilling mud inlet 320 may be fluidly connected to, for example, an outlet of a drilling mud pump via a connection; and the drilling mud outlet 325 may be fluidly connected to an inlet of a vibrator hose via a connection. Any suitable connection may be used for the drilling mud inlet 320 and the drilling mud outlet 325. For example, suitable connections include, but are not limited to, pipe fittings and welds. Connections are well known in the art. In an embodiment, the drilling mud inlet 320 may be fluidly connected to, for example, an outlet of a drilling mud pump via a weld; and the drilling mud outlet 325 may be fluidly connected to an inlet of a vibrator hose via a weld.

FIG. 4A illustrates an upper, cross-sectional view of an exemplary drilling mud screen system according to an embodiment of the present invention, showing a drilling mud screen. As shown in FIG. 4A, the drilling mud screen system 400 has a body 405 having a first end 410 and a second end 415, a drilling mud inlet 420 and a drilling mud outlet 425, a drilling mud screen access port 430, an end cap 435 and a drilling mud screen 440.

Any suitable connection may be used for the drilling mud inlet 420 and the drilling mud outlet 425. For example, suitable connections include, but are not limited to, pipe fittings and welds. Connections are well known in the art.

In an embodiment, the body 405 of the drilling mud screen system 400 may be constructed of any suitable material. For example, suitable materials include, but are not limited to, any alloy steel suitable for a drilling mud application. In an embodiment, the body 405 may be constructed of an American Iron and Steel Industry (AISI) 4130/75k yield or equivalent material. See e.g., FIG. 2. In an embodiment, the inner surface of the body 405 may be unpainted. See e.g., FIGS. 1 & 3A-3E. In an embodiment, the outer surface of the body 405 may be painted. Id.

In an embodiment, the body 405 has a first centerline 445 and a length 450. In an embodiment, the first centerline 445

32

extends through the center of the drilling mud screen access port 430 to the drilling mud outlet 425. The length 450 of the body 405 may be any suitable length. In an embodiment, the length 450 of the body 405 may be from about 30-inches to about 50-inches, and any range or value there between. In an embodiment, the length 450 may be about 40-inches.

In an embodiment, the body 405 has a second centerline 455. In an embodiment, the second centerline 455 extends through the center of the drilling mud inlet 420 to the first centerline 445.

In an embodiment, the first centerline 445 and the second centerline 455 form a first angle 460. In an embodiment, the first angle 460 may be from about 30-degrees to about 120-degrees, and any range or value there between. In an embodiment, the first angle 460 may be about 45-degrees. In an embodiment, the first angle 460 may be about 90-degrees.

In an embodiment, the first drilling mud inlet 420 may be offset from a first end 410 of the body 405. The first drilling mud inlet 420 may be offset from a first end 410 of the body 405 at any suitable distance. In an embodiment, the second centerline 455 may be offset from the first end 410 of the body 405 from about 9-inches to about 13-inches, and any range or value there between. In an embodiment, the second centerline 455 may be offset from the first end 410 of the body 405 about 11-inches.

In an embodiment, the drilling mud inlet 420 may have any suitable inner diameter 465; and the drilling mud inlet 420 may have any suitable outer diameter 470. In an embodiment, the inner diameter 465 of the drilling mud inlet 420 may be from about 3-inches to about 5-inches, and any range or value there between. In an embodiment, the inner diameter 465 of the drilling mud inlet 420 may be about 4-inches.

In an embodiment, the outer diameter 470 of the drilling mud inlet 420 may be from about 4.5-inches to about 6.5-inches, and any range or value there between. In an embodiment, the outer diameter 470 of the drilling mud inlet 420 may be about 5.5-inches.

In an embodiment, the body 405 has a first portion 475 and a second portion 480. In an embodiment, the first portion 475 of the body 405 may have a first inner diameter 485 and an outer diameter 495; and the second portion 480 of the body 405 may have a second inner diameter 490 and an outer diameter 495.

In an embodiment, the first inner diameter 485 of the body 405 may be from about 3-inches to about 5-inches, and any range or value there between. In an embodiment, the first inner diameter 485 of the body 405 may be about 4-inches.

In an embodiment, the second inner diameter 490 of the body 405 may be from about 3-inches to about 5-inches, and any range or value there between. In an embodiment, the second inner diameter 490 of the body 405 may be about 4-inches.

In an embodiment, a second portion 480 of the body 405 may have a second inner diameter 490 to provide a high flow rate of drilling mud through the drilling mud screen 440. In an embodiment, the second inner diameter 490 of the body 405 may be from about 3.5-inches to about 5.5-inches, and any range or value there between. In an embodiment, the second inner diameter 490 of the body 405 may be from about 4.5-inches to about 5.5-inches, and any range or value there between.

In an embodiment, the outer diameter 495 of the first portion 475 and/or the second portion 480 of the body 405 may be from about 5.5-inches to about 7.5-inches, and any range or value there between. In an embodiment, the outer

diameter **495** of the first portion **475** and/or the second portion **480** of the body **405** may be about 6.5-inches.

In an embodiment, the drilling mud outlet **425** may have any suitable inner diameter **465**; and the drilling mud outlet **425** may have any suitable outer diameter **470**. In an embodiment, the inner diameter **465** of the drilling mud outlet **425** may be from about 3-inches to about 5-inches, and any range or value there between. In an embodiment, the inner diameter **465** of the drilling mud outlet **425** may be about 4-inches.

In an embodiment, the outer diameter **470** of the drilling mud outlet **425** may be from about 4.5-inches to about 6.5-inches, and any range or value there between. In an embodiment, the outer diameter **470** of the drilling mud outlet **425** may be about 5.5-inches.

FIG. 4B illustrates a detailed view of A-A of FIG. 4A, showing an end cap **435** installed; and FIG. 4C illustrates a detailed view of A-A of FIGS. 4A-4B, showing the end cap **435** removed.

Drilling Mud Screen

The drilling mud screen **500** may be any suitable filter or screen capable of filtering or screening debris from drilling muds and completion fluids. For example, suitable drilling mud screens include, but are not limited to, drill screens and rod screens.

FIG. 5A illustrates an upper, cross-sectional view of a drilling mud screen according to an embodiment of the present invention, showing a filter **530** and an end cap **535**. As shown in FIG. 5A, the drilling mud screen **500** has a body **505** having a first end **510** and a second end **515**, a drilling mud inlet **520**, a drilling mud outlet **525**, a filter **530** and an end cap **535**.

In an embodiment, the drilling mud inlet **520** may be fluidly connected to, for example, an outlet of a drilling mud pump via a connection; and the drilling mud outlet **525** may be fluidly connected to an inlet of a vibrator hose via a connection. Any suitable connection may be used for the drilling mud inlet **520** and the drilling mud outlet **525**. For example, suitable connections include, but are not limited to, pipe fittings and welds. Connections are well known in the art. In an embodiment, the drilling mud inlet **520** may be fluidly connected to, for example, an outlet of a drilling mud pump via a weld; and the drilling mud outlet **525** may be fluidly connected to an inlet of a vibrator hose via a weld.

In an embodiment, the body **505** of the drilling mud screen **500** may be constructed of any suitable material. For example, suitable materials include, but are not limited to, any alloy steel or tool steel. In an embodiment, the body **505** may be constructed of an AISI 4145 or equivalent material. See e.g., FIGS. 5A-5E. In an embodiment, the body **505** may be constructed of tool steel or equivalent material.

In an embodiment, the body **505** of the drilling mud screen **500** may have a hardened coating to reduce washing (i.e., erosion) of the screen **500**. For example, suitable hardened coatings include, but are not limited to, any Carbide coating or equivalent. In an embodiment, the body **505** may have a Carbide coating with about 6% Cobalt binder or equivalent material.

In an embodiment, the body **505** of the drilling mud screen **500** has a centerline **545** and a length **550**. In an embodiment, the centerline **545** extends through the center of the drilling mud screen inlet **520** to the end cap **535**. The length **550** of the body **505** may be any suitable length. In an embodiment, the length **550** of the body **505** may be from about 20-inches to about 30-inches, and any range or value there between. In an embodiment, the length **550** may be about 25-inches.

In an embodiment, the drilling mud inlet **520** of the drilling mud screen **500** may have any suitable inner diameter **565**; and the drilling mud inlet **520** may have any suitable outer diameter **570**. In an embodiment, the inner diameter **565** of the drilling mud inlet **520** may be from about 3-inches to about 5-inches, and any range or value there between. In an embodiment, the inner diameter **565** of the drilling mud inlet **520** may be about 3.9-inches.

In an embodiment, the outer diameter **570** of the drilling mud inlet **520** may be from about 4-inches to about 6-inches, and any range or value there between. In an embodiment, the outer diameter **570** of the drilling mud inlet **520** may be about 4-inches.

In an embodiment, the body **505** of the drilling mud screen **500** has a first portion **575** and a second portion **580**. In an embodiment, the first portion **575** of the body **505** has a first length; and the second portion **580** of the body **505** has a second length. The first portion **575** and the second portion **580** may be any suitable length. In an embodiment, the first portion **575** may have a first length from about 6-inches to about 10-inches; and the second portion **580** may have a second length from about 14-inches to about 20-inches, and any range or value there between. In an embodiment, the first portion **575** may have a first length of about 7.5-inches; and the second portion **580** may have a second length of about 17.5-inches.

In an embodiment, a second portion **580** of the body **505** of the drilling mud screen **500** may have a filter **530**. In an embodiment, the filter **530** may comprise a plurality of rods spaced a distance apart to form a filter. In an embodiment, the distance may be less than a particle size (e.g., diameter) desired to be filtered from the drilling mud. Particle filtration is well known in the art.

In an embodiment, the filter **530** may comprise a formed sheet having drilled holes spaced a distance apart to form a filter. In an embodiment, the size of the holes (e.g., diameter) may be less than a particle size (e.g., diameter) desired to be filtered. Particle filtration is well known in the art.

In an embodiment, a second portion **580** of the body **505** of the drilling mud screen **500** may have a drilling mud outlet **525**. In an embodiment, the drilling mud outlet **525** may comprise a plurality of spaces (i.e., flow passages) between a plurality of rods. In an embodiment, the drilling mud outlet **525** may comprise a plurality of holes (i.e., flow passages) drilled in a formed sheet.

In an embodiment, a first end **510** of a first portion **575** of the body **505** of the drilling mud screen **500** may have a first inner diameter **585**; and a second end **515** of a second portion **580** of the body **505** may have a second inner diameter **590**.

In an embodiment, the first end **510** of the first portion **575** may be shaped to accept a puller/installer plate **975** of a drilling mud screen puller/installer tool **800, 900**, as discussed below. See e.g., FIGS. 5A, 8A & 9A.

In an embodiment, the body **505** and/or a filter **530** of the drilling mud screen **500** may have a tapered drilling mud flow path from a larger inner diameter to a smaller inner diameter to reduce washing (i.e., erosion) of the screen **500**.

In an embodiment, the first inner diameter **585** of the first end **510** of the body **505** of the drilling mud screen **500** may be from about 3-inches to about 5-inches, and any range or value there between. In an embodiment, the first inner diameter **585** of the first end **510** of the body **505** may be about 3.9-inches.

FIG. 5B illustrates a detailed view of A-A of FIG. 5A, showing an outlet of a first portion **575** of the body **505** and an inlet of the second portion **580** of the body **505**. In an

embodiment, an inner diameter of an outlet of the first portion 575 and an inlet of the second portion 590 of the body 505 may be from about 2-inches to about 3-inches, and any range or value there between. In an embodiment, the inner diameter of the outlet of the first portion 575 of the body 505 and the inlet of the second portion 590 of the body 505 may be about 2.5-inches.

In an embodiment, the outlet of the first portion 575 and/or the inlet of the second portion 590 of the body 505 may be shaped to accept a rounded end 875, 975 of a drilling mud screen puller/installer tool 800, 900. See e.g., FIGS. 5B, 8B & 9B. See also FIGS. 12B & 13B. In an embodiment, the inlet of the second portion 590 of the body 505 may have an inner shoulder to provide a pushing surface for the rounded end 875, 975 of the drilling mud screen puller/installer tool 800, 900. Id.

In an embodiment, the outlet of the first portion 575 and/or the inlet of the second portion 580 of the body 505 may have a means to engage 540 a drilling mud screen puller/installer tool 800, 900, as discussed below. See e.g., FIGS. 5A, 8A & 9A. The means to engage 540 may be any suitable means to accept, and provide a pulling surface for, the drilling mud screen puller/installer tool 800, 900. For example, a suitable means to engage 540 includes, but is not limited to, a "key" opening to rotationally engage an inner shoulder. In an embodiment, the outlet of the first portion 575 and/or the inlet of the second portion 590 of the body 505 may be shaped to accept a puller/installer plate 870, 970 of a drilling mud screen puller/installer tool 800, 900. See e.g., FIGS. 5B, 8B & 9B. See also FIGS. 12A, 13A & 29. In an embodiment, the inlet of the second portion 590 of the body 505 may have an inner shoulder to provide a pulling surface for the puller/installer plate 870, 970 of the drilling mud screen puller/installer tool 800, 900. Id.

In an embodiment, the second inner diameter 590 of the second end 515 of the body 505 of the drilling mud screen 500 may be from about 2-inches to about 3-inches, and any range or value there between. In an embodiment, the second inner diameter 590 of the second end 515 of the body 505 may be about 2.3-inches.

In an embodiment, the outer surface 595 of the first portion 575 of the body 505 of the drilling mud screen 500 may be adapted to engage one or more shoulders in an inner surface of the body 505. In an embodiment, a first shoulder and a second shoulder of the body 505 may be offset from a first end 510 of the body 505. Cf. FIGS. 4A & 5A. The first and second shoulders may be offset from the first end 510 of the body 505 at any suitable distance. In an embodiment, the first shoulder may be offset from the first end 510 of the body 505 from about 4-inches to about 8-inches; and the second shoulder may be offset from the first end 510 of the body 505 from about 5-inches to about 9-inches, and any range or value there between. In an embodiment, the first shoulder may be offset from the first end 510 of the body 505 about 4.8-inches; and the second shoulder may be offset from the first end 510 of the body 505 about 6.8-inches.

In an embodiment, the outer surface 595 of the body 505 of the drilling mud screen 500 may be sealed against an inner surface of the body 505 via an O-ring. Cf. FIGS. 4A & 5A. Any suitable O-ring may be used. For example, suitable O-rings include, but are not limited to, 300 Series O-rings. O-rings are well known in the art.

FIG. 5C illustrates a detailed view of B of FIG. 5A; and FIG. 5D illustrates a detailed view of C of FIG. 5A, both showing detailed views of a groove for an O-ring. In an embodiment, a groove for an O-ring may be offset from a first end 510 of the body 505 of the drilling mud screen 500.

The groove for the O-ring may be offset from the first end 510 of the body 505 at any suitable distance. In an embodiment, the groove for the O-ring may be offset from the first end 510 of the body 505 from about 4-inches to about 8-inches, and any range or value there between. In an embodiment, the groove for the O-ring may be offset from the first end 510 of the body 505 about 5.7-inches.

In an embodiment, the filter 530 may have a plurality of rods spaced a distance apart to form a filter, or, alternatively, 10 a formed sheet having drilled holes spaced a distance apart to form a filter. In an embodiment, the plurality of rods may be tapered from a larger outer diameter to a smaller outer diameter to encourage drilling mud flow to exit in straight lines through the drilling mud outlet 525 (i.e., through flow 15 passages between the plurality rods) to reduce washing (i.e., erosion) of the screen 500. In an embodiment, the filter 530 may have a plurality of straight rows of holes drilled in a formed sheet to encourage drilling mud flow to exit in straight rows of strings through the drilling mud outlet 525 (i.e., through straight flow passages of the drilled holes) to 20 reduce washing (i.e., erosion) of the screen 500.

In an embodiment, a first end of a filter 530 may be connected to a second end 515 of the body 505 via a connection; and a second end of a filter 530 may be connected to a first end of the end cap 535 via a connection. 25 Any suitable connection may be used for the drilling mud inlet 530. For example, suitable connections include, but are not limited to, welds. Connections are well known in the art. In an embodiment, the first end of the filter 530 may be connected to the second end 515 of the body 505 via a weld; and the second end of the filter 530 may be connected to the 30 first end of the end cap 535 via a weld.

In an embodiment, the first end of the filter 530 may fit into a first recess in the second end 515 of the body 505; and the second end of the filter may fit into a second recess in the first end of the end cap 535. In an embodiment, the first recess and the second recess may be a plurality of recessed 35 holes or a recessed groove. In an embodiment, the first recess and the second recess may be a plurality of recessed 40 holes.

In an embodiment, the filter 530 may be held together with a retaining ring. In an embodiment, the retaining ring may have a plurality of holes to hold the plurality of rods to form the filter 530. In an embodiment, the plurality of rods 45 may be connected to the plurality of holes in the retainer ring via a connection. Any suitable connection may be used for the drilling mud inlet 530. For example, suitable connections include, but are not limited to, welds. Connections are well known in the art. In an embodiment, the plurality of rods 50 may be connected to the plurality of holes in the retainer ring via a weld.

In an embodiment, the filter 530, including any retaining rings, of the drilling mud screen 500 may be constructed of any suitable material. For example, suitable materials 55 include, but are not limited to, any alloy steel. In an embodiment, the filter 530 may be constructed of 304 stainless steel material. See e.g., FIGS. 5A & 5E. In an embodiment, the filter 530 may have a hardened coating to reduce washing (i.e., erosion) of the screen 500.

In an embodiment, the end cap 535 of the drilling mud screen 500 has an inner surface 555. In an embodiment, the inner surface 555 of the end cap 535 of the drilling mud screen 500 may redirect the flow to reduce washing (i.e., erosion) of the screen 500. In an embodiment, the inner surface 555 of the end cap 535 of the drilling mud screen 500 forms an inverted cone relative to the second end 515 of the body 505 of the drilling mud screen 500 (i.e., an upstream

pointing cone) to redirect the flow. In an embodiment, the tip of the inverted cone may have a rounded or squared shape.

In an embodiment, the body 505 of the drilling mud screen 500 has a centerline 545 and a length 550. In an embodiment, the centerline 545 extends through the center of the drilling mud screen inlet 520 to the end cap 535. In an embodiment, the centerline 545 of the body 505 of the drilling mud screen 500 and the inner surface 555 of the end cap 535 form an angle 560. In an embodiment, the angle 560 may be from about 30-degrees to about 60-degrees, and any range or value there between. In an embodiment, the angle 560 may be from about 35-degrees to about 45-degrees, and any range or value there between.

In an embodiment, the end cap 535 of the drilling mud screen 500 may be constructed of any suitable material. For example, suitable materials include, but are not limited to, any alloy steel. In an embodiment, the end cap 535 may be constructed of 304 stainless steel material. See e.g., FIGS. 5A & 5E. In an embodiment, the end cap 535 of the drilling mud screen 500 may have a hardened coating to reduce washing (i.e., erosion) of the screen 500. For example, suitable hardened coatings include, but are not limited to, any Carbide coating or equivalent. In an embodiment, the end cap 535 may have a Carbide coating with about 6% Cobalt binder or equivalent material.

FIG. 5E illustrates an upper, right side perspective view of the drilling mud screen of FIG. 5A. As shown in FIG. 5E, the drilling mud screen 500 has a body 505 having a first end 510 and a second end 515, a drilling mud inlet 520, a drilling mud outlet 525, a filter 530 and an end cap 535. In an embodiment, the body 505 of the drilling mud screen 500 has a first portion 575 and a second portion 580.

Optional Plug for Single-Piece Body

As discussed above, the single-piece body 405 for the exemplary drilling mud screen system of FIGS. 1-4 has a drilling mud flow passage from the drilling mud inlet 420 (through the drilling mud inlet 520 of the drilling mud screen 440, through the drilling mud outlet 525 of the drilling mud screen 440) and to the drilling mud outlet 425. See e.g., FIGS. 4A & 5.

The single-piece body 405, however, also has a drilling mud flow passage into a void between the drilling mud inlet 420 and the mud screen access port 430. Id.

FIG. 14 illustrates a cross-sectional view of the exemplary drilling mud screen of FIG. 4, showing an optional plug installed in the drilling mud screen system. As shown in FIGS. 4 and 14, the drilling mud screen system 400, 1400 has a body 405, 1405 having a first end 410, 1410 and a second end 415, 1415, a drilling mud inlet 420, 1420 and a drilling mud outlet 425, 1425, a drilling mud screen access port 430, 1430, an end cap 435, 1435, a drilling mud screen 440, 1440 and a plug 14100. In an embodiment, the optional plug 14100 has a flow surface 14105.

In an embodiment, the optional plug 14100 fills the void between the drilling mud inlet 420, 1420 and the mud screen access port 430, 1430; and the flow surface 14105 of the optional plug 14100 directs the drilling mud from the drilling mud inlet 420, 1420 of the drilling mud screen system 400, 1400 to the drilling mud inlet 520 of the drilling mud screen 440, 1440, resulting in increased flow efficiency and decreased erosion.

In an embodiment, the plug 14100 may be constructed of any suitable material. For example, suitable materials include, but are not limited to, any alloy steel suitable for a drilling mud application. In an embodiment, the plug 14100 may be constructed of an American Iron and Steel Industry (AISI) 4130/75k yield or equivalent material.

In an embodiment, the plug 14100 may have any suitable outer diameter to fit within the body 405, 1405. In an embodiment, the outer diameter of the plug 14100 may be from about 3-inches to about 5-inches, and any range or value there between. In an embodiment, the outer diameter of the plug 14100 may be about 3.9-inches.

In an embodiment, the optional plug 14100 has a flow surface 14105 to direct the drilling mud from the drilling mud inlet 420, 1420 of the drilling mud screen system 400, 1400 to the drilling mud inlet 520 of the drilling mud screen 440, 1440. See e.g., FIGS. 4A & 5. In an embodiment, the flow surface 14105 may have any suitable shape to direct the drilling mud from the drilling mud inlet of the drilling mud screen system to the drilling mud inlet of the drilling mud screen. Suitable shapes include, but are not limited to, a backward "J" shape, a curved shape, an "L" shape and any combination or variation thereof, as discussed further below.

FIG. 15A illustrates an upper, right perspective view of an optional plug with a backward "J" shaped flow surface according to an embodiment of the present invention; and FIG. 15B illustrates a cross-sectional view of the optional plug with the backward "J" shaped flow surface of FIG. 15A. As shown in FIGS. 15A and 15B, the optional plug 1500 has a body 1505 having a first end 1510 and a second end 1515, a flow surface 1520, an optional cavity 1530 and an optional port 1560.

In an embodiment, the first end 1510 of the body 1505 may have a means to engage 1525 a drilling mud screen puller/installer tool 800. See e.g., FIGS. 8A, 15A-15B & 18A-18B. The means to engage 1525 may be any suitable means to accept, and provide a pulling surface for, the drilling mud screen puller/installer tool 800. For example, a suitable means to engage 1525 includes, but is not limited to, a "key" opening to rotationally engage an inner shoulder.

In an embodiment, the first end 1510 of the plug 1500 may have an optional cavity 1530 extending towards, but not through, the flow surface 1520 of the plug 1500.

In an embodiment, the first end 1510 of the plug 1500 may have an optional port 1560 extending from an outer surface of the plug 1500 into the optional cavity 1530.

In an embodiment, the first end 1510 of the plug 1500 may have any suitable inner diameter 1535 of the optional cavity 1530. In an embodiment, the inner diameter 1535 of the optional cavity 1530 may be from about 1-inch to about 3-inches, and any range or value there between. In an embodiment, the inner diameter 1535 of the optional cavity 1530 may be about 2-inches.

In an embodiment, the plug 1500 may have any suitable outer diameter 1540. In an embodiment, the outer diameter 1540 of the plug 1500 may be from about 3-inches to about 5-inches, and any range or value there between. In an embodiment, the outer diameter 1540 of the plug 1500 may be about 3.9-inches.

In an embodiment, the body 1505 has a centerline 1545, a first length 1550 and a second length 1555. In an embodiment, the first length 1550 of the body 1505 may be any suitable length. In an embodiment, the first length 1550 of the body 1505 may be from about 6-inches to about 10-inches, and any range or value there between. In an embodiment, the length 1550 may be about 8-inches.

In an embodiment, the second length 1555 of the body 1505 may be any suitable length. In an embodiment, the second length 1555 may be from about 8-inches to about 14-inches, and any range or value there between. In an embodiment, the second length 1555 may be about 11.5-inches.

In an embodiment, the second end 1515 of the plug 1500 may have a flow surface 1520. In an embodiment, the flow surface 1520 may have any suitable shape to direct the drilling mud from the drilling mud inlet of the drilling mud screen system to the drilling mud inlet of the drilling mud screen. Suitable shapes include, but are not limited to, a backward "J" shape, a curved shape, an "L" shape and any combination or variation thereof, as discussed further below. In an embodiment, the flow surface 1520 may have a backward "J" shape. See e.g., FIG. 15B.

FIG. 16A illustrates an upper, right perspective view of an optional plug with a curved flow surface according to an embodiment of the present invention; and FIG. 16B illustrates a cross-sectional view of the optional plug with the curved flow surface of FIG. 16A. As shown in FIGS. 16A and 16B, the optional plug 1600 has a body 1605 having a first end 1610 and a second end 1615, a flow surface 1620, an optional cavity 1630 and an optional port 1660.

In an embodiment, the first end 1610 of the body 1605 may have a means to engage 1625 a drilling mud screen puller/installer tool 800. See e.g., FIGS. 8A, 16A-16B, 18A-18B & 29. The means to engage 1625 may be any suitable means to accept, and provide a pulling surface for, the drilling mud screen puller/installer tool 800. For example, a suitable means to engage 1625 includes, but is not limited to, a "key" opening to rotationally engage an inner shoulder.

In an embodiment, the first end 1610 of the plug 1600 may have an optional cavity 1630 extending towards, but not through, the flow surface 1620 of the plug 1600.

In an embodiment, the first end 1610 of the plug 1600 may have an optional port 1660 extending from an outer surface of the plug 1600 into the optional cavity 1630.

In an embodiment, the first end 1610 of the plug 1600 may have any suitable inner diameter 1635 of the optional cavity 1630. In an embodiment, the inner diameter 1635 of the optional cavity 1630 may be from about 1-inch to about 3-inches, and any range or value there between. In an embodiment, the inner diameter 1635 of the optional cavity 1630 may be about 2-inches.

In an embodiment, the plug 1600 may have any suitable outer diameter 1640. In an embodiment, the outer diameter 1640 of the plug 1600 may be from about 3-inches to about 5-inches, and any range or value there between. In an embodiment, the outer diameter 1640 of the plug 1600 may be about 3.9-inches.

In an embodiment, the body 1605 has a centerline 1645, a first length 1650 and a second length 1655. In an embodiment, the first length 1650 of the body 1605 may be any suitable length. In an embodiment, the first length 1650 of the body 1605 may be from about 6-inches to about 10-inches, and any range or value there between. In an embodiment, the length 1650 may be about 8-inches.

In an embodiment, the second length 1655 of the body 1605 may be any suitable length. In an embodiment, the second length 1655 may be from about 8-inches to about 15-inches, and any range or value there between. In an embodiment, the second length 1655 may be about 12-inches.

In an embodiment, the second end 1615 of the plug 1600 may have a flow surface 1620. In an embodiment, the flow surface 1620 may have any suitable shape to direct the drilling mud from the drilling mud inlet of the drilling mud screen system to the drilling mud inlet of the drilling mud screen. Suitable shapes include, but are not limited to, a backward "J" shape, a curved shape, an "L" shape and any

combination or variation thereof, as discussed further below. In an embodiment, the flow surface 1620 may have a curved shape. See e.g., FIG. 16B.

FIG. 17A illustrates an upper, right perspective view of an optional plug with an "L" flow surface according to an embodiment of the present invention; and FIG. 17B illustrates a cross-sectional view of an optional plug with an "L" flow surface of FIG. 17A. As shown in FIGS. 17A and 17B, the optional plug 1700 has a body 1705 having a first end 1710 and a second end 1715, a flow surface 1720, an optional cavity 1730 and an optional port 1760.

In an embodiment, the first end 1710 of the body 1705 may have a means to engage 1725 a drilling mud screen puller/installer tool 800. See e.g., FIGS. 8A, 17A-17B, 18A-18B & 29. The means to engage 1725 may be any suitable means to accept, and provide a pulling surface for, the drilling mud screen puller/installer tool 800. For example, a suitable means to engage 1725 includes, but is not limited to, a "key" opening to rotationally engage an inner shoulder.

In an embodiment, the first end 1710 of the plug 1700 may have an optional cavity 1730 extending towards, but not through, the flow surface 1720 of the plug 1700.

In an embodiment, the first end 1710 of the plug 1700 may have an optional port 1760 extending from an outer surface of the plug 1700 into the optional cavity 1730.

In an embodiment, the first end 1710 of the plug 1700 may have any suitable inner diameter 1735 of the optional cavity 1730. In an embodiment, the inner diameter 1735 of the optional cavity 1730 may be from about 1-inch to about 3-inches, and any range or value there between. In an embodiment, the inner diameter 1735 of the optional cavity 1730 may be about 2-inches.

In an embodiment, the plug 1700 may have any suitable outer diameter 1740. In an embodiment, the outer diameter 1740 of the plug 1700 may be from about 3-inches to about 5-inches, and any range or value there between. In an embodiment, the outer diameter 1740 of the plug 1700 may be about 3.9-inches.

In an embodiment, the body 1705 has a centerline 1745, a first length 1750 and a second length 1755. In an embodiment, the first length 1750 of the body 1705 may be any suitable length. In an embodiment, the first length 1750 of the body 1705 may be from about 6-inches to about 10-inches, and any range or value there between. In an embodiment, the length 1750 may be about 8-inches.

In an embodiment, the second length 1755 of the body 1705 may be any suitable length. In an embodiment, the second length 1755 may be from about 8-inches to about 15-inches, and any range or value there between. In an embodiment, the second length 1755 may be about 12-inches.

In an embodiment, the second end 1715 of the plug 1700 may have a flow surface 1720. In an embodiment, the flow surface 1720 may have any suitable shape to direct the drilling mud from the drilling mud inlet of the drilling mud screen system to the drilling mud inlet of the drilling mud screen. Suitable shapes include, but are not limited to, a backward "J" shape, a curved shape, an "L" shape and any combination or variation thereof, as discussed further below. In an embodiment, the flow surface 1720 may have an "L" shape. See e.g., FIG. 17B.

Two-Piece Body

FIG. 6A illustrates an image of a drilling mud screen system according to an embodiment of the present invention, showing a two-piece body for the system.

As shown in FIG. 6A, the drilling mud screen system 600 has a first body 605a having a first end 610a and a second end 615a, a first drilling mud inlet 620a, a first drilling mud outlet 625a, a first drilling mud screen access port 630a, and an end cap 635. The drilling mud screen system 600 has a second body 605b having a first end 610b and a second end 615b, a second drilling mud inlet 620b and a second drilling mud outlet 625b, and a second drilling mud screen access port 630b.

In an embodiment, the first drilling mud inlet 620a may be fluidly connected to, for example, an outlet of a drilling mud pump via a connection; and the second drilling mud outlet 625b may be fluidly connected to an inlet of a vibrator hose via a connection. Any suitable connection may be used for the first drilling mud inlet 620a and second drilling mud outlet 625b. For example, suitable connections include, but are not limited to, pipe fittings and welds. Connections are well known in the art. In an embodiment, the first drilling mud inlet 620a may be fluidly connected to, for example, an outlet of a drilling mud pump via a weld; and the second drilling mud outlet 625b may be fluidly connected to an inlet of a vibrator hose via a weld.

As shown in FIG. 6A, the drilling mud screen access port 630 of the drilling mud screen system 600 may be closed with an end cap 635 via a connection. Any suitable connection may be used. For example, suitable connections include, but are not limited to, pipe fittings. Connections are well known in the art.

In an embodiment, the drilling mud screen access port 630 of the drilling mud screen system 600 may be sealed with an end cap 635 via an O-ring. Any suitable O-ring may be used. For example, suitable O-rings include, but are not limited to, 300 Series O-rings. O-rings are well known in the art.

In an embodiment, the end cap 635 of the drilling mud screen system 600 may comprise a cap, an O-ring and a pipe collar. In an embodiment, the end cap may be a five-inch 1002 WECO cap with an O-ring.

FIG. 6B illustrates an image of the exemplary drilling mud screen system of FIG. 6A, showing a second drilling mud outlet 625b.

FIG. 6C illustrates an image of the exemplary drilling mud screen system of FIGS. 6A-6B.

FIG. 6D illustrates an image of the exemplary drilling mud screen system of FIGS. 6A-6C, showing a detailed view of a first body 605a of the drilling mud screen system 600. In an embodiment, the first body 605a may be a five-inch 1002 WECO Y-housing.

Standard Single Inlet and Optional Reduced Angle Inlet Version

FIG. 7A illustrates an upper, cross-sectional view of a drilling mud screen system 700 according to an embodiment of the present invention, showing a standard single-inlet drilling mud system.

FIG. 19 illustrates a cross-sectional view of the drilling mud screen system in a monitoring configuration 1900 according to an embodiment of the present invention, showing an optional transducer subassembly 19100.

FIG. 21A illustrates an upper view of a mud screen system 2100 according to an embodiment of the present invention, showing an optional two-piece body for the system; and FIG. 21B illustrates a detailed, cross-sectional view of A-A of FIG. 21A, showing an entry angle of about 30 degrees.

FIG. 23 illustrates a cross-sectional view of a mud screen system 2300 according to an embodiment of the present invention, showing an optional drilling mud screen insert 23105 inserted into a drilling mud screen 2340.

FIG. 41A illustrates a cross-sectional view of an exemplary drilling mud screen system 4100 according to an embodiment of the invention, showing a reversed drilling mud screen 4140.

As shown in FIGS. 7A, 19, 23 and 41A, the drilling mud screen system 700, 1900, 2100, 2300, 4100 has a first body 705a, 1905a, 2105a, 2305a, 4105a having a first end 710a, 1910a, 2110a, 2310a, 4110a and a second end 715a, 1915a, 2115a, 2315a, 4115a, a first drilling mud inlet 720a, 1920a, 2120a, 2320a, 4120a and a first drilling mud outlet 725a, 1925a, 2125a, 2325a, 4125a, an end cap 735, 1935, 2135, 2335, 4135, and a first drilling mud screen access port 730a, 1930a, 2130a, 2330a, 4130a. The drilling mud screen system 700, 1900, 2100, 2300, 4100 has a second body 705b, 1905b, 2105b, 2305b, 4105b having a first end 710b, 1910b, 2110b, 2310b, 4110b and a second end 715b, 1915b, 2115b, 2315b, 4115b, a second drilling mud inlet 720b, 1920b, 2120b, 2320b, 4120b, a second drilling mud outlet 725b, 1925b, 2125b, 2325b, 4125b, a second drilling mud screen access port 730b, 1930b, 2130b, 2330b, 4130b, and a third access port 4130c.

In an embodiment, the first drilling mud inlet 720a, 1920a, 2120a, 2320a may be fluidly connected to, for example, an outlet of a drilling mud pump via a connection; and the second drilling mud outlet 725b, 1925b, 2125b, 2325b may be fluidly connected to an inlet of a vibrator hose via a connection. Any suitable connection may be used for the first drilling mud inlet 720a, 1920a, 2120a, 2320a and second drilling mud outlet 725b, 1925b, 2125b, 2325b. For example, suitable connections include, but are not limited to, pipe fittings and welds. Connections are well known in the art. In an embodiment, the first drilling mud inlet 720a, 1920a, 2120a, 2320a may be fluidly connected to, for example, an outlet of a drilling mud pump via a weld; and the second drilling mud outlet 725b, 1925b, 2125b, 2325b may be fluidly connected to an inlet of a vibrator hose via a weld.

In an embodiment, the first body 705a, 1905a, 2105a, 2305a, 4105a and the second body 705b, 1905b, 2105b, 2305b, 4105b may be fluidly connected by a connection. Any suitable connection may be used for the first body 705a, 1905a, 2105a, 2305a, 4105a and the second body 705b, 1905b, 2105b, 2305b, 4105b. For example, suitable connections include, but are not limited to, pipe fittings. Connections are well known in the art. In an embodiment, the first body 705a, 1905a, 2105a, 2305a, 4105a and the second body 705b, 1905b, 2105b, 2305b, 4105b may be fluidly connected by a union. In an embodiment, the union may be a five-inch 1002 WECO union.

In an embodiment, the first body 705a, 1905a, 2105a, 2305a, 4105a and the second body 705b, 1905b, 2105b, 2305b, 4105b of the drilling mud screen system 700, 1900, 2100, 2300, 4100 may be constructed of any suitable material. For example, suitable materials include, but are not limited to, any alloy steel suitable for a drilling mud application. In an embodiment, the first body 705a, 1905a, 2105a, 2305a, 4105a and the second body 705b, 1905b, 2105b, 2305b, 4105b may be constructed of an AISI 4130/75k yield or equivalent material. See e.g., FIGS. 6A-6D. In an embodiment, the inner surface of the first body 705a, 1905a, 2105a, 2305a, 4105a and the second body 705b, 1905b, 2105b, 2305b, 4105b may be unpainted. See e.g., FIG. 6D. In an embodiment, the outer surface of the first body 705a, 1905a, 2105a, 2305a, 4105a and the second body 705b, 1905b, 2105b, 2305b, 4105b may be painted. See e.g., FIGS. 6A-6D.

In an embodiment, the drilling mud screen system 700, 1900, 2100, 2300, 4100 has a length 750, 1950, 2150, 2350, 4150. The length 750, 1950, 2150, 2350, 4150 may be any suitable length. In an embodiment, the length 750, 1950, 2150, 2350, 4150 may be from about 40-inches to about 80-inches, and any range or value there between. In an embodiment, the length 750, 1950, 2150, 2350, 4150 may be about 56-inches.

In an embodiment, the first body 705a, 1905a, 2105a, 2305a, 4105a has a first centerline 745a, 1945a, 2145a, 2345a, 4145a and a first length 750a, 1950a, 2150a, 2350a, 4150a. In an embodiment, the first centerline 745a, 1945a, 2145a, 2345a, 4145a extends through the center of the first drilling mud screen access port 730a, 1930a, 2130a, 2330a, 4130a to the first drilling mud outlet 725a, 1925a, 2125a, 2325a, 4125a. The first length 750a, 1950a, 2150a, 2350a, 4150a of the first body 705a, 1905a, 2105a, 2305a, 4105a may be any suitable length. In an embodiment, the first length 750a, 1950a, 2150a, 2350a, 4150a of the first body 705a, 1905a, 2105a, 2305a, 4105a may be from about 20-inches to about 40-inches, and any range or value there between. In an embodiment, the first length 750a, 1950a, 2150a, 2350a, 4150a may be about 27-inches or 30-inches.

In an embodiment, the first body 705a, 1905a, 2105a, 2305a, 4105a has a second centerline 755, 1955, 2155, 2355, 4155 and a third length 750c, 1950c, 2150c, 2350c, 4150c. In an embodiment, the second centerline 755, 1955, 2155, 2355, 4155 extends through the center of the first drilling mud inlet 720a, 1920a, 2120a, 2320a, 4120a to the first centerline 745a, 1945a, 2145a, 2345a, 4145a of the first body 705a, 1905a, 2105a, 2305a, 4105a. The third length 750c, 1950c, 2150c, 2350c, 4150c of the first body 705a, 1905a, 2105a, 2305a, 4105a may be any suitable length.

In an embodiment, the third length 750c, 1950c, 2350c, 4150c of the first body 705a, 1905a, 2305a, 4105a may be from about 10-inches to about 20-inches, and any range or value there between. In an embodiment, the third length 750c, 1950c, 2350c, 4150c may be about 14-inches or 16-inches.

In an embodiment, the third length 2150c of the first body 2105a may be from about 20-inches to about 40-inches, and any range or value there between. In an embodiment, the third length 2150c may be about 25-inches or 30-inches.

In an embodiment, the first centerline 745a, 1945a, 2145a, 2345a, 4145a and the second centerline 755, 1955, 2155, 2355, 4155 of the first body 705a, 1905a, 2105a, 2305a, 4105a form a first angle 760, 1960, 2160, 2360, 4160.

In an embodiment, the first angle 760, 1960, 2360, 4160 may be from about 30-degrees to about 120-degrees, and any range or value there between. In an embodiment, the first angle 760, 1960, 2360, 4160 may be from about 45-degrees to about 60-degrees. In an embodiment, the first angle 760, 1960, 2360, 4160 may be about 90-degrees.

In an embodiment, the first body 2105a may be modified to reduce the entry angle 2160 of the first drilling mud inlet 2120, resulting in increased flow efficiency and decreased erosion. In an embodiment, the first angle 2160 may be from about 20-degrees to about 120-degrees, and any range or value there between. In an embodiment, the first angle 2160 may be about 30-degrees.

In an embodiment, the first drilling mud inlet 720a, 1920a, 2120a, 2320a, 4120a may be offset from a first end 710a, 1910a, 2110a, 2310a, 4110a of the first body 705a, 1905a, 2105a, 2305a, 4105a. The first drilling mud inlet 720a, 1920a, 2120a, 2320a, 4120a may be offset from a first end 710a, 1910a, 2110a, 2310a, 4110a of the first body

705a, 1905a, 2105a, 2305a, 4105a at any suitable distance. In an embodiment, the second centerline 755, 1955, 2155, 2355, 4155 may be offset from the first end 710a, 1910a, 2110a, 2310a, 4110a of the first body 705a, 1905a, 2105a, 2305a, 4105a from about 15-inches to about 20-inches, and any range or value there between. In an embodiment, the second centerline 755, 1955, 2155, 2355, 4155 may be offset from the first end 710a, 1910a, 2110a, 2310a, 4110a of the first body 705a, 1905a, 2105a, 2305a, 4105a about 18-inches.

In an embodiment, the first drilling mud inlet 720a, 1920a, 2120a, 2320a, 4120a may have any suitable first inner diameter 765a, 1965a, 2165a, 2365a; and the first drilling mud inlet 720a, 1920a, 2120a, 2320a, 4120a may have any suitable first outer diameter 770a, 1970a, 2170a, 2370a. In an embodiment, the first inner diameter 765a, 1965a, 2165a, 2365a of the first drilling mud inlet 720a, 1920a, 2120a, 2320a, 4120a may be from about 3-inches to about 5-inches, and any range or value there between. In an embodiment, the first inner diameter 765a, 1965a, 2165a, 2365a of the first drilling mud inlet 720a, 1920a, 2120a, 2320a, 4120a may be about 4-inches.

In an embodiment, the first outer diameter 770a, 1970a, 2170a, 2370a of the first drilling mud inlet 720a, 1920a, 2120a, 2320a, 4120a may be from about 4.5-inches to about 6.5-inches, and any range or value there between. In an embodiment, the first outer diameter 770a, 1970a, 2170a, 2370a of the first drilling mud inlet 720a, 1920a, 2120a, 2320a, 4120a may be about 5.5-inches.

In an embodiment, the second body 705b, 1905b, 2105b, 2305b, 4105b has a second centerline 745b, 1945b, 2145b, 2345b, 4145b and a second length 750b, 1950b, 2150b, 2350b, 4150b. In an embodiment, the second centerline 745b, 1945b, 2145b, 2345b, 4145b extends through the center of the second drilling mud screen access port 730b, 1930b, 2130b, 2330b, 4130b (and the second drilling mud inlet 720b, 1920b, 2120b, 2320b, 4120b) to the second drilling mud outlet 725b, 1925b, 2125b, 2325b, 4125b. The second length 750b, 1950b, 2150b, 2350b, 4150b of the second body 705b, 1905b, 2105b, 2305b, 4105b may be any suitable length. In an embodiment, the second length 750b, 1950b, 2150b, 2350b, 4150b of the second body 705b, 1905b, 2105b, 2305b, 4105b may be from about 20-inches to about 40-inches, and any range or value there between. In an embodiment, the second length 750b, 1950b, 2150b, 2350b, 4150b may be about 25-inches.

In an embodiment, the second drilling mud inlet 720b, 1920b, 2120b, 2320b, 4120b may have any suitable second inner diameter 765b, 1965b, 2165b, 2365b; and the second drilling mud inlet 720b, 1920b, 2120b, 2320b, 4120b may have any suitable second outer diameter 770b, 1970b, 2170b, 2370b. In an embodiment, the second inner diameter 765b, 1965b, 2165b, 2365b of the second drilling mud inlet 720b, 1920b, 2120b, 2320b, 4120b may be from about 3-inches to about 5-inches, and any range or value there between. In an embodiment, the second inner diameter 765b, 1965b, 2165b, 2365b of the second drilling mud inlet 720b, 1920b, 2120b, 2320b, 4120b may be about 4-inches.

In an embodiment, the second outer diameter 770b, 1970b, 2170b, 2370b of the second drilling mud inlet 720b, 1920b, 2120b, 2320b, 4120b may be from about 4.5-inches to about 6.5-inches, and any range or value there between. In an embodiment, the second outer diameter 770b, 1970b, 2170b, 2370b of the second drilling mud inlet 720b, 1920b, 2120b, 2320b, 4120b may be about 5.5-inches.

In an embodiment, the first body 705a, 1905a, 2105a, 2305a, 4105a has a first portion 775, 1975, 2175, 2375, 4175

and the second body 705b, 1905b, 2105b, 2305b, 4105b has a second portion 780, 1980, 2180, 2380, 4180. In an embodiment, the first portion 775, 1975, 2175, 2375, 4175 of the first body 705a, 1905a, 2105a, 2305a, 4105a may have a first inner diameter 785, 1985, 2185, 2385 and an outer diameter 795, 1995, 2195, 2395; and the second portion 780, 1980, 2180, 2380, 4180 of the second body 705b, 1905b, 2105b, 2305b, 4105b may have a second inner diameter 790, 1990, 2190, 2390 and an outer diameter 795, 1995, 2195, 2395.

In an embodiment, the first inner diameter 785, 1985, 2185, 2385 of the first body 705a, 1905a, 2105a, 2305a, 4105a may be from about 3-inches to about 5-inches, and any range or value there between. In an embodiment, the first inner diameter 785, 1985, 2185, 2385 of the first body 705a, 1905a, 2105a, 2305a, 4105a may be about 4-inches.

In an embodiment, the first drilling mud outlet 725a, 1925a, 2125a, 2325a, 4125a may have any suitable first inner diameter 765a, 1965a, 2165a, 2365a; and the first drilling mud outlet 725a, 1925a, 2135a, 2325a, 4125a may have any suitable first outer diameter 770a, 1970a, 2170a, 2370a. In an embodiment, the first inner diameter 765a, 1965a, 2165a, 2365a of the first drilling mud outlet 725a, 1925a, 2125a, 2325a, 4125a may be from about 3-inches to about 5-inches, and any range or value there between. In an embodiment, the first inner diameter 765a, 1965a, 2165a, 2365a of the first drilling mud outlet 725a, 1925a, 2125a, 2325a, 4125a may be about 4-inches.

In an embodiment, the first outer diameter 770a, 1970a, 2170a, 2370a of the first drilling mud outlet 725a, 1925a, 2125a, 2325a, 4125a may be from about 4.5-inches to about 6.5-inches, and any range or value there between. In an embodiment, the first outer diameter 770a, 1970a, 2170a, 2370a of the first drilling mud outlet 725a, 1925a, 2125a, 2325a, 4125a may be about 5-inches.

In an embodiment, the second inner diameter 790, 1990, 2190, 2390 of the second body 705b, 1905b, 2105b, 2305b, 4105b may be from about 3-inches to about 5-inches, and any range or value there between. In an embodiment, the second inner diameter 790, 1990, 2190, 2390 of the second body 705b, 1905b, 2105b, 2305b, 4105b may be about 4-inches.

In an embodiment, a second portion 780, 1980, 2180, 2380 of the second body 705b, 1905b, 2105b, 2305b, 4105b may have a second inner diameter 790, 1990, 2190, 2390 to provide a high flow rate of drilling mud through the drilling mud screen 740, 1940, 2140, 2340, 4140. In an embodiment, the second inner diameter 790, 1990, 2190, 2390 of the second body 705b, 1905b, 2105b, 2305b, 4105b may be from about 3.5-inches to about 5.5-inches, and any range or value there between. In an embodiment, the second inner diameter 790, 1990, 2190, 2390 of the second body 705b, 1905b, 2105b, 2305b, 4105b may be from about 4.5-inches to about 5.5-inches, and any range or value there between.

In an embodiment, the first outer diameter 795, 1995, 2195, 2395 of the first portion 775, 1975, 2175, 2375, 4175 of the first body 705a, 1905a, 2105a, 2305a, 4105a and/or the second portion 780, 1980, 2180, 2380, 4180 of the second body 705b, 1905b, 2105b, 2305b, 4105b may be from about 5.5-inches to about 7.5-inches, and any range or value there between. In an embodiment, the first outer diameter 795, 1995, 2195, 2395 of the first portion 775, 1975, 2175, 2375, 4175 of the first body 705a, 1905a, 2105a, 2305a, 4105a and/or the second portion 780, 1980, 2180, 2380, 4180 of the second body 705b, 1905b, 2105b, 2305b, 4105b may be about 6.5-inches.

In an embodiment, the second drilling mud outlet 725b, 1925b, 2125b, 2325b, 4125b may have any suitable second inner diameter 765b, 1965b, 2165b, 2365b; and the second drilling mud outlet 725b, 1925b, 2125b, 2325b, 4125b may have any suitable second outer diameter 770b, 1970b, 2170b, 2370b. In an embodiment, the second inner diameter 765b, 1965b, 2165b, 2365b of the second drilling mud outlet 725b, 1925b, 2125b, 2325b, 4125b may be from about 3-inches to about 5-inches, and any range or value there between. In an embodiment, the second inner diameter 765b, 1965b, 2165b, 2365b of the second drilling mud outlet 725b, 1925b, 2125b, 2325b, 4125b may be about 4-inches.

In an embodiment, the second outer diameter 770b, 1970b, 2170b, 2370b of the second drilling mud outlet 725b, 1925b, 2125b, 2325b, 4125b may be from about 4.5-inches to about 6.5-inches, and any range or value there between. In an embodiment, the second outer diameter 770b, 1970b, 2170b, 2370b of the second drilling mud outlet 725b, 1925b, 2125b, 2325b, 4125b may be about 5.5-inches.

Optional Double Inlet

FIG. 7B illustrates an upper, cross-sectional view of a drilling mud screen system according to an embodiment of the present invention, showing an optional double-inlet drilling mud system.

As shown in FIG. 7B, the drilling mud screen system 700 has a first body 705a having a first end 710a and a second end 715a, a first drilling mud inlet 720a, an optional first drilling mud inlet 720a' and a first drilling mud outlet 725a, an end cap 735, and a first drilling mud screen access port 730a. The drilling mud screen system 700 has a second body 705b having a first end 710b and a second end 715b, a second drilling mud inlet 720b, a second drilling mud outlet 725b, and a second drilling mud screen access port 730b.

In an embodiment, the first drilling mud inlet 720a and the optional first drilling mud inlet 720a' may be fluidly connected to, for example, an outlet of a drilling mud pump via a connection; and the second drilling mud outlet 725b may be fluidly connected to an inlet of a vibrator hose via a connection. Any suitable connection may be used for the first drilling mud inlet 720a, the optional first drilling mud inlet 720a' and the second drilling mud outlet 725b. For example, suitable connections include, but are not limited to, pipe fittings and welds. Connections are well known in the art. In an embodiment, the first drilling mud inlet 720a and the optional first drilling mud inlet 720a' may be fluidly connected to, for example, an outlet of a drilling mud pump via a weld; and the second drilling mud outlet 725b may be fluidly connected to an inlet of a vibrator hose via a weld.

In an embodiment, the first body 705a and the second body 705b may be fluidly connected by a connection. Any suitable connection may be used for the first body 705a and the second body 705b. For example, suitable connections include, but are not limited to, pipe fittings. Connections are well known in the art. In an embodiment, the first body 705a and the second body 705b may be fluidly connected by a union. In an embodiment, the union may be a five-inch 1002 WECO union.

In an embodiment, the first body 705a and the second body 705b of the drilling mud screen system 700 may be constructed of any suitable material. For example, suitable materials include, but are not limited to, any alloy steel suitable for a drilling mud application. In an embodiment, the first body 705a and the second body 705b may be constructed of an AISI 4130/75k yield or equivalent material. See e.g., FIGS. 6A-6D. In an embodiment, the inner surface of the first body 705a and the second body 705b may be unpainted. See e.g., FIG. 6D. In an embodiment, the outer

surface of the first body 705a and the second body 705b may be painted. See e.g., FIGS. 6A-6D.

In an embodiment, the drilling mud screen system has a length 750. The length 750 may be any suitable length. In an embodiment, the length 750 may be from about 40-inches to about 80-inches, and any range or value there between. In an embodiment, the length 750 may be about 56-inches.

In an embodiment, the first body 705a has a first centerline 745a and a first length 750a. In an embodiment, the first centerline 745a extends through the center of the first drilling mud screen access port 730a to the first drilling mud outlet 725a. The first length 750a of the first body 705a may be any suitable length. In an embodiment, the first length 750a of the first body 705a may be from about 20-inches to about 40-inches, and any range or value there between. In an embodiment, the first length 750a may be about 30-inches.

In an embodiment, the first body 705a has a second centerline 755 and a third length 750c. In an embodiment, the second centerline 755 extends through the center of the first drilling mud inlet 720a to the first centerline 745a of the first body 705a. The third length 750c of the first body 705a may be any suitable length. In an embodiment, the third length 750c of the first body 705a may be from about 10-inches to about 20-inches, and any range or value there between. In an embodiment, the third length 750c may be about 14-inches or 16-inches.

In an embodiment, the first body 705a has a second centerline 755 and a third length 750c, and an optional second centerline 755' and an optional third length 750c'. In an embodiment, the second centerline 755 extends through the center of the first drilling mud inlet 720a to the first centerline 745a of the first body 705a. In an embodiment, the optional second centerline 755' extends through the center of the optional first drilling mud inlet 720a' to the first centerline 745a of the first body 705a. The third length 750c of the first body 705a may be any suitable length; and the optional third length 750c' of the first body 705a may be any suitable length.

In an embodiment, the third length 750c of the first body 705a may be from about 10-inches to about 20-inches, and any range or value there between. In an embodiment, the third length 750c may be about 14-inches or 16-inches.

In an embodiment, the optional third length 750c' of the first body 705a may be from about 10-inches to about 20-inches, and any range or value there between. In an embodiment, the optional third length 750c' may be about 14-inches or 16-inches.

In an embodiment, the third length 750c may be the same as the optional third length 750c'. In an embodiment, the third length 750c may be different from the optional third length 750c'.

In an embodiment, the first centerline 745a and the second centerline 755 of the first body 705a form a first angle 760. In an embodiment, the first angle 760 may be from about 30-degrees to about 120-degrees, and any range or value there between. In an embodiment, the first angle 760 may be from about 45-degrees to about 60-degrees. In an embodiment, the first angle 760 may be about 90-degrees.

In an embodiment, the first drilling mud inlet 720a may be offset from a first end 710a of the first body 705a. The first drilling mud inlet 720a may be offset from a first end 710a of the first body 705a at any suitable distance. In an embodiment, the second centerline 755 may be offset from the first end 710a of the first body 705a from about 15-inches to about 20-inches, and any range or value there

between. In an embodiment, the second centerline 755 may be offset from the first end 710a of the first body 705a about 18-inches.

In an embodiment, the first drilling mud inlet 720a may have any suitable first inner diameter 765a; and the first drilling mud inlet 720a may have any suitable first outer diameter 770a. In an embodiment, the first inner diameter 765a of the first drilling mud inlet 720a' may be from about 3-inches to about 5-inches, and any range or value there between. In an embodiment, the first inner diameter 765a of the first drilling mud inlet 720a may be about 4-inches.

In an embodiment, the first centerline 745a and the optional second centerline 755' of the first body 705a form an optional first angle 760'. In an embodiment, the optional first angle 760' may be from about 30-degrees to about 120-degrees, and any range or value there between. In an embodiment, the optional first angle 760' may be from about 45-degrees to about 60-degrees. In an embodiment, the optional first angle 760' may be about 90-degrees.

In an embodiment, the first angle 760 may be the same as the optional first angle 760'. In an embodiment, the first angle 760 may be different from the optional first angle 760'.

In an embodiment, the optional first drilling mud inlet 720a' may be offset from a first end 710a of the first body 705a. The optional first drilling mud inlet 720a' may be offset from a first end 710a of the first body 705a at any suitable distance. In an embodiment, the optional first centerline 755' may be offset from the first end 710a of the first body 705a from about 15-inches to about 20-inches, and any range or value there between. In an embodiment, the optional first centerline 755' may be offset from the first end 710a of the first body 705a about 18-inches.

In an embodiment, the optional second centerline 755' of the optional first drilling mud inlet 720a' may be offset from the second centerline 755 of the first drilling mud inlet 720a radially about the first centerline 745a of the first body 705a to form an optional second angle 760''. In an embodiment, the optional second angle 760'' may be from about 30 degrees to about 120 degrees, and any range or value there between. In an embodiment, the optional second angle 760'' may be from about 45-degrees to about 120-degrees. In an embodiment, the optional second angle 760'' may be from about 90-degrees to about 120-degrees. In an embodiment, the optional second angle 760'' may be about 120-degrees. See e.g., FIG. 7B.

In an embodiment, the optional first drilling mud inlet 720a' may have any suitable optional first inner diameter 765a'; and the optional first drilling mud inlet 720a' may have any suitable optional first outer diameter 770a'. In an embodiment, the optional first inner diameter 765a' of the optional first drilling mud inlet 720a' may be from about 3-inches to about 5-inches, and any range or value there between. In an embodiment, the optional first inner diameter 765a' of the optional first drilling mud inlet 720a' may be about 4-inches.

In an embodiment, the first outer diameter 770a of the first drilling mud inlet 720a may be from about 4.5-inches to about 6.5-inches, and any range or value there between. In an embodiment, the first outer diameter 770a of the first drilling mud inlet 720a may be about 5.5-inches.

In an embodiment, the optional first outer diameter 770a' of the optional first drilling mud inlet 720a' may be from about 4.5-inches to about 6.5-inches, and any range or value there between. In an embodiment, the optional first outer diameter 770a' of the optional first drilling mud inlet 720a' may be about 5.5-inches.

In an embodiment, the second body 705b has a second centerline 745b and a second length 750b. In an embodiment, the second centerline 745b extends through the center of the second drilling mud screen access port 730b (and the second drilling mud inlet 720b) to the second drilling mud outlet 725b. The second length 750b of the second body 705b may be any suitable length. In an embodiment, the second length 750b of the second body 705b may be from about 20-inches to about 40-inches, and any range or value there between. In an embodiment, the second length 750b may be about 25-inches.

In an embodiment, the second drilling mud inlet 720b may have any suitable second inner diameter 765b; and the second drilling mud inlet 720b may have any suitable second outer diameter 770b. In an embodiment, the second inner diameter 765b of the second drilling mud inlet 720b may be from about 3-inches to about 5-inches, and any range or value there between. In an embodiment, the second inner diameter 765b of the second drilling mud inlet 720b may be about 4-inches.

In an embodiment, the second outer diameter 770b of the second drilling mud inlet 720b may be from about 4.5-inches to about 6.5-inches, and any range or value there between. In an embodiment, the second outer diameter 770b of the second drilling mud inlet 720b may be about 5.5-inches.

In an embodiment, the first body 705a has a first portion 775 and the second body 705b has a second portion 780. In an embodiment, the first portion 775 of the first body 705a may have a first inner diameter 785 and an outer diameter 795; and the second portion 780 of the second body 705b may have a second inner diameter 790 and an outer diameter 795.

In an embodiment, the first inner diameter 785 of the first body 705a may be from about 3-inches to about 5-inches, and any range or value there between. In an embodiment, the first inner diameter 785 of the first body 705a may be about 4-inches.

In an embodiment, the first drilling mud outlet 725a may have any suitable first inner diameter 765a; and the first drilling mud outlet 725a may have any suitable first outer diameter 770a. In an embodiment, the first inner diameter 765a of the first drilling mud outlet 725a may be from about 3-inches to about 5-inches, and any range or value there between. In an embodiment, the first inner diameter 765a of the first drilling mud outlet 725a may be about 4-inches.

In an embodiment, the first outer diameter 770a of the first drilling mud outlet 725a may be from about 4.5-inches to about 6.5-inches, and any range or value there between. In an embodiment, the first outer diameter 770a of the first drilling mud outlet 725a may be about 5-inches.

In an embodiment, the second inner diameter 790 of the second body 705b may be from about 3-inches to about 5-inches, and any range or value there between. In an embodiment, the second inner diameter 790 of the second body 705b may be about 4-inches.

In an embodiment, a second portion 780 of the second body 705b may have a second inner diameter 790 to provide a high flow rate of drilling mud through the drilling mud screen 740. In an embodiment, the second inner diameter 790 of the second body 705b may be from about 3.5-inches to about 5.5-inches, and any range or value there between. In an embodiment, the second inner diameter 790 of the second body 705b may be from about 4.5-inches to about 5.5-inches, and any range or value there between.

In an embodiment, the first outer diameter 795 of the first portion 775 of the first body 705a and/or the second portion

780 of the second body 705b may be from about 5.5-inches to about 7.5-inches, and any range or value there between. In an embodiment, the first outer diameter 795 of the first portion 775 of the first body 705a and/or the second portion 780 of the second body 705b may be about 6.5-inches.

In an embodiment, the second drilling mud outlet 725b may have any suitable second inner diameter 765b; and the second drilling mud outlet 725b may have any suitable second outer diameter 770b. In an embodiment, the second inner diameter 765b of the second drilling mud outlet 725b may be from about 3-inches to about 5-inches, and any range or value there between. In an embodiment, the second inner diameter 765b of the second drilling mud outlet 725b may be about 4-inches.

In an embodiment, the second outer diameter 770b of the second drilling mud outlet 725b may be from about 4.5-inches to about 6.5-inches, and any range or value there between. In an embodiment, the second outer diameter 770b of the second drilling mud outlet 725b may be about 5.5-inches.

Two-Piece Piston Body

In an embodiment, a piston-style drilling mud screen system may be used to provide easier access to the drilling mud screen and to reduce the foot-print of the drilling mud screen system.

FIG. 30A illustrates a cross-sectional view of an exemplary piston-style drilling mud screen system 3000 according to an embodiment of the present invention, showing a two-piece piston body for the system mounted on a skid 3000a; FIG. 30B illustrates an upper, left perspective view of the exemplary piston-style drilling mud screen system 3000 of FIG. 30A, showing the piston-style drilling mud screen system in a closed position; FIG. 30C illustrates an upper, left perspective view of the exemplary piston-style drilling mud screen system 3000 of FIGS. 30A-30B, showing the piston-style drilling mud screen system in an unlatched position; FIG. 30D illustrates an upper, left perspective view of the exemplary piston-style drilling mud screen system 3000 of FIGS. 30A and 30C, showing the piston-style drilling mud screen system an unlatched and rotated position for removal of a drilling mud screen; FIG. 30E illustrates an upper, left perspective view of the exemplary piston-style drilling mud screen system 3000 of FIGS. 30A and 30D, showing the piston-style drilling mud screen system an unlatched and rotated position after removal of the drilling mud screen 3040; FIG. 30F illustrates a detailed view of an exemplary positive lock mechanism for the piston-style drilling mud screen system 3000 of FIGS. 30A-30E, showing a spring-loaded lock mechanism; and FIG. 30G illustrates a detailed view of an exemplary breech lock connection for the exemplary piston-style drilling mud screen system 3000 of FIGS. 30A-30F, showing a quarter turn breech lock connection.

As shown in FIGS. 30A-30G, the piston-style drilling mud screen system 3000 comprises a first subassembly 30000a, a first body 3005a, a lock system 3010 (discussed below), a second body 3005b and a second subassembly 30000b. The piston-style drilling mud screen system 3000 has a first subassembly 30000a having a first end 3010a and a second end 3015a, a first inlet 30020a of the first subassembly 30000a and a first outlet 30025a of the first subassembly 30000a. The piston-style drilling mud screen system 3000 has a first body 3005a having a first end 3010a and a second end 3015a, a first drilling mud inlet 3020a of the first body 3005a and a first drilling mud outlet 3025a of the first body 3005a (and a first drilling mud screen access port 3030a of the first body 3005a). The piston-style drilling

mud screen system **3000** has a second body **3005b** having a first end **3010b** and a second end **3015b**, a second drilling mud inlet **3020b** of the second body **3005b** (and a second drilling mud screen access port **3030b** of the second body **3005b**) and a second drilling mud outlet **3025b** of the second body **3005b**. The piston-style drilling mud screen system **3000** has a second subassembly **30000b** having a first end **30010b** and a second end **30015b**, a second inlet **30020b** of the second subassembly **30000b** and a second outlet **30025b** of the second subassembly **30000b**.

In an embodiment, the first drilling mud inlet **30020a** of the first subassembly **30000a** may be fluidly connected to, for example, an outlet of a drilling mud pump via a connection; and the second drilling mud outlet **30025b** of the second subassembly **30000b** may be fluidly connected to an inlet of a vibrator hose via a connection. Any suitable connection may be used for the first drilling mud inlet **30020a** of the first subassembly **30000a** and the second drilling mud outlet **30025b** of the second subassembly **30000b**. For example, suitable connections include, but are not limited to, pipe fittings and welds. Connections are well known in the art. In an embodiment, the first drilling mud inlet **30020a** of the first subassembly **30000a** may be fluidly connected to, for example, an outlet of a drilling mud pump via a weld; and the second drilling mud outlet **30025b** of the second subassembly **30000b** may be fluidly connected to an inlet of a vibrator hose via a weld.

In an embodiment, the first drilling mud inlet **3020a** of the first body **3005a** may be fluidly connected to the first drilling mud outlet **30025a** of the first subassembly **30000a** via a connection; and the second drilling mud outlet **3025b** of the second body **3005b** may be fluidly connected to the second drilling mud inlet **30020b** of the second subassembly **30000b** via a connection. Any suitable connection may be used for the first drilling mud inlet **3020a** of the first body **3005a** and second drilling mud outlet **3025b** of the second body **3005b**. For example, suitable connections include, but are not limited to, pipe fittings and quarter-turn breech lock connections. In an embodiment, the first drilling mud inlet **3020a** of the first body **3005a** may be fluidly connected to, for example, a first drilling mud outlet **30025a** of a first subassembly **30000a** via a quarter-turn breech lock connection; and the second drilling mud outlet **3025b** of the second body **3005b** may be fluidly connected to a second drilling mud inlet **30020b** of the second subassembly **30000b** via a quarter-turn breech lock connection.

In an embodiment, the first drilling mud outlet **3025a** of the first body **3005a** may be fluidly connected to the second drilling mud inlet **3020b** of the second body **3005b** via a sleeve extending from a first end **3010b** of the second body **3005b**. See e.g., FIG. 30A. The sleeve may be integral to the second body **3005b** or fluidly connected to the second body **3005b**. In an embodiment, a first end of the sleeve of the second body **3005b** may be inserted into the first drilling mud outlet **3025a** of the first body **3005a**. In an embodiment, the first body **3005a** and/or the second body **3005b** may be sealed via an O-ring. Any suitable O-ring may be used. For example, suitable O-rings include, but are not limited to, 300 Series O-rings. O-rings are well known in the art.

In an embodiment, the first drilling mud outlet **3025a** of the first body **3005a** may be fluidly connected to the second drilling mud inlet **3020b** of the second body **3005b** via a sleeve extending from a second end **3015a** of the first body **3005a**. The sleeve may be integral to the first body **3005a** or fluidly connected to the first body **3005a**. In an embodiment, a second end of the sleeve of the first body **3005a** may be inserted into the second drilling mud inlet **3020b** of the second body **3005b**.

second body **3005b**. In an embodiment, the first body **3005a** and/or the second body **3005b** may be sealed via an O-ring. Any suitable O-ring may be used. For example, suitable O-rings include, but are not limited to, 300 Series O-rings. O-rings are well known in the art.

In an embodiment, the first drilling mud outlet **3025a** of the first body **3005a** may be fluidly connected to the second drilling mud inlet **3020b** of the second body **3005b** via a union. In an embodiment, the union may be a lock system **30100**. In an embodiment, the first body **3005a** and/or the second body **3005b** may be sealed with the lock system **30100** via an O-ring. Any suitable O-ring may be used. For example, suitable O-rings include, but are not limited to, 300 Series O-rings. O-rings are well known in the art.

In an embodiment, the first drilling mud outlet **3025a** of the first body **3005** may be fluidly connected to a first inlet **30125a** of a first body **30105a** of the lock system **30100**. In an embodiment, the first body **3005a** may be sealed with the lock system **30100** via an O-ring. Any suitable O-ring may be used. For example, suitable O-rings include, but are not limited to, 300 Series O-rings. O-rings are well known in the art.

In an embodiment, a first outlet **30125a** of the first body **30105a** of the lock system **30100** may be fluidly connected to a second inlet **30120b** of a second body **30105b** of the lock system **30100**. In an embodiment, the first body **30105a** of the lock system **30100** may be sealed with the second body **30105b** of the lock system **30100** via an O-ring. Any suitable O-ring may be used. For example, suitable O-rings include, but are not limited to, 300 Series O-rings. O-rings are well known in the art.

In an embodiment, the second outlet **30125b** of the second body **30105b** of the lock system **30100** may be fluidly connected to the second drilling mud inlet **3020b** of the second body **3005b**. In an embodiment, the second body **3005b** may be sealed with the lock system **30100** via an O-ring. Any suitable O-ring may be used. For example, suitable O-rings include, but are not limited to, 300 Series O-rings. O-rings are well known in the art.

In an embodiment, the first subassembly **30000a** and the second subassembly **30000b** of the drilling mud screen system **3000** may be constructed of any suitable material. For example, suitable materials include, but are not limited to, any alloy steel suitable for a drilling mud application. In an embodiment, the first subassembly **30000a** and the second subassembly **30000b** may be constructed of an AISI 4130/75k yield or equivalent material. See e.g., FIGS. 30A-30E. In an embodiment, the inner surface of the first subassembly **30000a** and the second subassembly **30000b** may be unpainted. In an embodiment, the outer surface of the first subassembly **30000a** and the second assembly **30000b** may be painted.

In an embodiment, the first body **3005a** and the second body **3005b** of the drilling mud screen system **3000** may be constructed of any suitable material. For example, suitable materials include, but are not limited to, any alloy steel suitable for a drilling mud application. In an embodiment, the first body **3005a** and the second body **3005b** may be constructed of an AISI 4130/75k yield or equivalent material. See e.g., FIGS. 30A-30E. In an embodiment, the inner surface of the first body **3005a** and the second body **3005b** may be unpainted. In an embodiment, the outer surface of the first body **3005a** and the second body **3005b** may be painted.

In an embodiment, the drilling mud screen system **3000** has a length **3050**. The length **3050** may be any suitable length. In an embodiment, the length **3050** may be from

about 40-inches to about 80-inches, and any range or value there between. In an embodiment, the length **3050** may be about 41 inches or about 42-inches.

In an embodiment, the drilling mud screen system **3000**, including a first subassembly **30000a** and a second subassembly **30000b**, has a length **30050**. The length **30050** may be any suitable length. In an embodiment, the length **30050** may be from about 40-inches to about 100-inches, and any range or value there between. In an embodiment, the length **30050** may be about 60-inches.

In an embodiment, the first subassembly **30000a** has a first centerline **30045a** and a first length **30050a**. In an embodiment, the first centerline **30045a** extends through the center of the first drilling mud screen inlet **30020a** of the first subassembly **30000a** to the first drilling mud outlet **30025a** of the first subassembly **30000a** (and the first drilling mud screen inlet **3020a** of the first body **3005a**). The first length **30050a** of the first subassembly **30000a** may be any suitable length. In an embodiment, the first length **30050a** of the first subassembly **30000a** may be from about 4-inches to about 10-inches, and any range or value there between. In an embodiment, the first length **30050a** of the first subassembly **30000a** may be about 6-inches.

In an embodiment, the first drilling mud inlet **30020a** of the first subassembly **30000a** may have any suitable first inner diameter **30065a**; and the first drilling mud inlet **30020a** of the first subassembly **30000a** may have any suitable first outer diameter **30070a**. In an embodiment, the first inner diameter **30065a** of the first drilling mud inlet **30020a** may be from about 3-inches to about 5-inches, and any range or value there between. In an embodiment, the first inner diameter **30065a** of the first drilling mud inlet **30020a** may be about 4-inches.

In an embodiment, the first outer diameter **30070a** of the first drilling mud inlet **30020a** may be from about 4.5-inches to about 6.5-inches, and any range or value there between. In an embodiment, the first outer diameter **30070a** of the first drilling mud inlet **30020a** may be about 5.5-inches.

In an embodiment, the second subassembly **30000b** has a second centerline **30045b** and a second length **30050b**. In an embodiment, the second centerline **30045b** extends through the center of the second drilling mud screen inlet **30020b** of the second subassembly **30000b** (and the second drilling mud outlet **3025b** of the second body **3005b**) to the second drilling mud outlet **30020b** of the second subassembly **30000b**. The second length **30050b** of the second subassembly **30000b** may be any suitable length. In an embodiment, the second length **30050b** of the second subassembly **30000b** may be from about 4-inches to about 10-inches, and any range or value there between. In an embodiment, the second length **30050b** of the second subassembly **30000b** may be about 6-inches.

In an embodiment, the second drilling mud inlet **30020b** of the second subassembly **30000b** may have any suitable second inner diameter **30065b**; and the second drilling mud inlet **30020b** of the second subassembly **30000b** may have any suitable second outer diameter **30070b**. In an embodiment, the second inner diameter **30065b** of the second drilling mud inlet **30020b** may be from about 3-inches to about 5-inches, and any range or value there between. In an embodiment, the second inner diameter **30065b** of the second drilling mud inlet **30020b** may be about 4-inches.

In an embodiment, the second outer diameter **30070b** of the second drilling mud inlet **30020b** may be from about 4.5-inches to about 6.5-inches, and any range or value there

between. In an embodiment, the second outer diameter **30070b** of the second drilling mud inlet **30020b** may be about 5.5-inches.

In an embodiment, the first body **3005a** has a first centerline **3045a** and a first length **3050a**. In an embodiment, the first centerline **3045a** extends through the center of the first drilling mud screen inlet **3020a** to the first drilling mud outlet **3025a** (and the first drilling mud screen access port **3030a**). The first length **3050a** of the first body **3005a** may be any suitable length. In an embodiment, the first length **3050a** of the first body **3005a** may be from about 15-inches to about 40-inches, and any range or value there between. In an embodiment, the first length **3050a** may be about 16.5-inches.

In an embodiment, the first drilling mud inlet **3020a** may have any suitable first inner diameter **3065a**; and the first drilling mud inlet **3020a** may have any suitable first outer diameter **3070a**. In an embodiment, the first inner diameter **3065a** of the first drilling mud inlet **3020a** may be from about 3-inches to about 5-inches, and any range or value there between. In an embodiment, the first inner diameter **3065a** of the first drilling mud inlet **3020a** may be about 4-inches.

In an embodiment, the first outer diameter **3070a** of the first drilling mud inlet **3020a** may be from about 4.5-inches to about 6.5-inches, and any range or value there between. In an embodiment, the first outer diameter **3070a** of the first drilling mud inlet **3020a** may be about 5.5-inches.

In an embodiment, the first drilling mud outlet **3025a** may have any suitable first inner diameter **3065a**; and the first drilling mud outlet **3025a** may have any suitable first outer diameter **3070a**. In an embodiment, the first inner diameter **3065a** of the first drilling mud outlet **3025a** may be from about 3-inches to about 5-inches, and any range or value there between. In an embodiment, the first inner diameter **3065a** of the first drilling mud outlet **3025a** may be about 4-inches.

In an embodiment, the first outer diameter **3070a** of the first drilling mud outlet **3025a** may be from about 4.5-inches to about 6.5-inches, and any range or value there between. In an embodiment, the first outer diameter **3070a** of the first drilling mud outlet **3025a** may be about 5.5-inches.

In an embodiment, the second body **3005b** has a second centerline **3045b** and a second length **3050b**. In an embodiment, the second centerline **3045b** extends through the center of the second drilling mud screen access port **3030b** (and the second drilling mud inlet **3020b**) to the second drilling mud outlet **3025b**. The second length **3050b** of the second body **3005b** may be any suitable length. In an embodiment, the second length **3050b** of the second body **3005b** may be from about 15-inches to about 40-inches, and any range or value there between. In an embodiment, the second length **3050b** may be about 18-inches or about 19-inches.

In an embodiment, the second drilling mud inlet **3020b** may have any suitable second inner diameter **3065b**; and the second drilling mud inlet **3020b** may have any suitable second outer diameter **3070b**. In an embodiment, the second inner diameter **3065b** of the second drilling mud inlet **3020b** may be from about 3-inches to about 5-inches, and any range or value there between. In an embodiment, the second inner diameter **3065b** of the second drilling mud inlet **3020b** may be about 4-inches.

In an embodiment, the second outer diameter **3070b** of the second drilling mud inlet **3020b** may be from about 4.5-inches to about 6.5-inches, and any range or value there

between. In an embodiment, the second outer diameter **3070b** of the second drilling mud inlet **3020b** may be about 5.5-inches.

In an embodiment, the second drilling mud outlet **3025b** may have any suitable second inner diameter **3065b**; and the second drilling mud outlet **3025b** may have any suitable second outer diameter **3070b**. In an embodiment, the second inner diameter **3065b** of the second drilling mud outlet **3025b** may be from about 3-inches to about 5-inches, and any range or value there between. In an embodiment, the second inner diameter **3065b** of the second drilling mud outlet **3025b** may be about 4-inches.

In an embodiment, the second outer diameter **3070b** of the second drilling mud outlet **3025b** may be from about 4.5-inches to about 6.5-inches, and any range or value there between. In an embodiment, the second outer diameter **3070b** of the second drilling mud outlet **3025b** may be about 5.5-inches.

Lock System

The piston-style drilling mud screen system **3000** has a lock system **30100**. The lock system **30100** has a first lock **30100a**, and a second lock **30100b**, a first body **30105a** of the lock system **30100** having a first end **30105a** and a second end **30105b**, a second body **30105b** of the lock system **30100** having a first end **30110a** and a second end **30110b**.

In an embodiment, the first end **30110a** of the first body **30105a** of the lock system **30100** (and the second end **3015a** of the first body **3005a**) may be adapted to receive the first lock **30100a**. See e.g., FIG. 30F. In an embodiment, the first lock **30100a** may extend through the first end **30110a** of the first body **30105a** of the lock system and engage the second end **3015a** of the first body **3005a** when the system **3000** is closed.

The first lock **30100a** may be any suitable positive locking mechanism. For example, a suitable first lock **30100a** includes, but is not limited to, a spring-loaded lock. In an embodiment, the first lock **30100a** may be a spring-loaded lock. See e.g., FIG. 30F.

In an embodiment, the second end **3015a** of the first body **3005a** may be disposed through the first end **30110a** of the first body **30105a** of the lock system **30100** such that the second end **3015a** of the first body **3005a** is held by a first lip at the first end **30110a** of the first body **30105a** of the lock system **30100**. See e.g., FIG. 30A.

In an embodiment, the second end **3015a** of the first body **3005a** and the first end **30110b** of the first body **30105a** of the lock system **30100** may be sealed via an O-ring. Any suitable O-ring may be used. For example, suitable O-rings include, but are not limited to, 300 Series O-rings. O-rings are well known in the art.

In an embodiment, the second end **30115b** of the second body **30105b** of the lock system **30100** (and the second end **3015b** of the second body **3005b**) may be adapted to receive the second lock **30100b**. See e.g., FIG. 30F. In an embodiment, the second lock **30100b** may extend through the second end **30115b** of the second body **30105b** of the lock system **30100** and engage the second body **3005b** when the system is closed.

The second lock **30100b** may be any suitable positive locking mechanism. For example, a suitable second lock **30100b** includes, but is not limited to, a spring-loaded lock. In an embodiment, the second lock **30100b** may be a spring-loaded lock. See e.g., FIG. 30F.

In an embodiment, the first end **3010b** of the second body **3005b** may be disposed through the second end **30115b** of the second body **30105b** of the lock system **30100** such that

the first end **3010b** of the second body **3005b** is held by a second lip at or near the second end **30115b** of the second body **30105b** of the lock system **30100**.

In an embodiment, the first end **3010b** of the second body **3005b** and the second end **30115b** of the second body **30105b** of the lock system **30100** may be sealed via an O-ring. Any suitable O-ring may be used. For example, suitable O-rings include, but are not limited to, 300 Series O-rings. O-rings are well known in the art.

In an embodiment, the second end **30115a** of the first body **30105a** and the first end **30110b** of the second body **30105b** of the lock system **30100** may be attached by a connection. Any suitable connection may be used for the second end **30115a** of the first body **30105a** and the first end **30110b** of the second body **30105b** of the lock system **30100**. For example, suitable connections include, but are not limited to, pipe fittings and threads. Connections are well known in the art. In an embodiment, the first end **30110b** of second body **30105b** of the lock system **30100** may be threaded into the second end **30115a** of the first body **30105a** of the lock system **30100**. In an embodiment, the second end **30115a** of the first body **30105a** of the lock system **30100** may be threaded into the first end **30110b** of the second body **30105b** of the lock system **30100**.

In an embodiment, the second end **30115a** of the first body **30105a** and the first end **30110b** of the second body **30105b** of the lock system **30100** may be sealed via an O-ring. Any suitable O-ring may be used. For example, suitable O-rings include, but are not limited to, 300 Series O-rings. O-rings are well known in the art.

In an embodiment, the first body **30105a** and the second body **30105b** of the lock system **30100** may be constructed of any suitable material. For example, suitable materials include, but are not limited to, any alloy steel suitable for a drilling mud application. In an embodiment, the first body **30105a** and the second body **30105b** may be constructed of an AISI 4130/75k yield or equivalent material. See e.g., FIGS. 30A-30E. In an embodiment, the inner surface of the first body **30105a** and the second body **30105b** may be unpainted. In an embodiment, the outer surface of the first body **30105a** and the second body **30105b** may be painted.

In an embodiment, the lock system **30100** has a length **30150**. The length **30150** may be any suitable length. In an embodiment, the length **30150** may be from about 8-inches to about 20-inches, and any range or value there between. In an embodiment, the length **30150** may be about 11-inches or about 12-inches.

In an embodiment, the first body **30105a** has a first centerline **30145a** and a first length **30150a**. In an embodiment, the first centerline **30145a** extends through the center of the first inlet **30120a** to the first outlet **30125a**. The first length **30150a** of the first body **30105a** may be any suitable length. In an embodiment, the first length **30150a** of the first body **30105a** may be from about 4-inches to about 15-inches, and any range or value there between. In an embodiment, the first length **30150a** may be about 9-inches or about 10-inches.

In an embodiment, the first inlet **30120a** of the first body **30105a** may have any suitable first inner diameter **30165a**; and the first inlet **30120a** of the first body **30105a** may have any suitable first outer diameter **30170a**. In an embodiment, the first inner diameter **30065a** of the first inlet **30020a** may be from about 4.5-inches to about 6.5-inches (e.g., outer diameter of first body **3005a**), and any range or value there between. In an embodiment, the first inner diameter **30165a** of the first inlet **30120a** may be about 5.5-inches.

In an embodiment, the first outer diameter **30170a** of the first inlet **30020a** may be from about 6-inches to about 8-inches, and any range or value there between. In an embodiment, the first outer diameter **30170a** of the first inlet **30120a** may be about 7-inches.

In an embodiment, the first body **30105a** may have any suitable first inner diameter **30185a**; and the first body **30105a** may have any suitable first outer diameter **30190a**. In an embodiment, the first inner diameter **30170a** of the first body **30105a** may be from about 4.5-inches to about 6-inches (e.g., outer diameter of second body **3005b**), and any range or value there between. In an embodiment, the first inner diameter **30170a** of the first body **30105a** may be about 5.5-inches.

In an embodiment, the first outer diameter **30190a** of the first body **30105a** may be from about 6-inches to about 8-inches, and any range or value there between. In an embodiment, the first outer diameter **30090a** of the first body **30105a** may be about 7-inches.

In an embodiment, the first outlet **30125a** of the first body **30105a** may have any suitable first inner diameter **31100a**; and the first outlet **30125a** of the first body **30105a** may have any suitable first outer diameter **30195a**. In an embodiment, the first inner diameter **31100a** of the first outlet **30125a** may be from about 4.5-inches to about 6.5-inches (e.g., outer diameter of first body **3005a**), and any range or value there between. In an embodiment, the first inner diameter **31100a** of the first outlet **30125a** may be about 5.5-inches.

In an embodiment, the second body **30105b** has a second centerline **30145b** and a second length **30150b**. In an embodiment, the second centerline **30145b** extends through the center of the second inlet **30120b** to the second outlet **30125b**. The second length **30150b** of the second body **30105b** may be any suitable length. In an embodiment, the second length **30150b** of the second body **30105b** may be from about 4-inches to about 10-inches, and any range or value there between. In an embodiment, the second length **30150b** may be about 6-inches or about 7-inches.

In an embodiment, the second inlet **30120b** of the second body **30105b** may have any suitable second inner diameter **31100b**; and the second inlet **30120b** of the second body **30105b** may have any suitable second outer diameter **30195b**. In an embodiment, the second inner diameter **31100b** of the second inlet **30020b** may be from about 4.5-inches to about 6.5-inches (e.g., outer diameter of second body **3005b**), and any range or value there between. In an embodiment, the second inner diameter **31100b** of the second inlet **30120b** may be about 5.5-inches.

In an embodiment, the second body **30105b** may have any suitable second inner diameter **30185b**; and the second body **30105b** may have any suitable second outer diameter **30190b**. In an embodiment, the second inner diameter **30170b** of the second body **30105b** may be from about 4.5-inches to about 6.5-inches (e.g., outer diameter of second body **3005b**), and any range or value there between. In an embodiment, the second inner diameter **30170b** of the second body **30105b** may be about 5.5-inches.

In an embodiment, the second outer diameter **30190b** of the second body **30105b** may be from about 6-inches to about 8-inches, and any range or value there between. In an embodiment, the second outer diameter **30090b** of the second body **30105b** may be about 7-inches.

In an embodiment, the second outlet **30125b** of the second body **30105b** may have any suitable second inner diameter **30165b**; and the second outlet **30125b** of the second body **30105b** may have any suitable second outer diameter **30170b**. In an embodiment, the second inner diameter

30165b of the second outlet **30125b** may be from about 4.5-inches to about 6.5-inches (e.g., outer diameter of second body **3005b**), and any range or value there between. In an embodiment, the second inner diameter **30165b** of the second outlet **30125b** may be about 5.5-inches.

In an embodiment, the second outer diameter **30170b** of the second outlet **30125b** may be from about 6-inches to about 8-inches, and any range or value there between. In an embodiment, the second outer diameter **30070b** of the second outlet **30125b** may be about 7-inches.

Alternative Two-Piece Piston Body

In an embodiment, an alternative piston-style drilling mud screen system may be used to provide easier access to the drilling mud screen and to reduce the foot-print of the drilling mud screen system. This piston-style drilling mud screen system uses pipe fitting connections instead of breech-lock connections and a union system instead of a lock system

FIGS. 33A-33C illustrate a cross-sectional view of an exemplary piston-style drilling mud screen system **3300** according to an embodiment of the present invention, showing an alternative two-piece piston body for the system (after installation of a drilling mud screen **3340**) mounted on an alternative skid **3300a**; FIG. 34A illustrates an upper, right perspective view of the exemplary piston-style drilling mud screen system **3400**, showing the piston-style drilling mud screen system in a closed position mounted on an alternative skid **3400a**; and FIG. 34B illustrates a lower, left perspective view of the exemplary piston-style drilling mud screen system **3400** of FIG. 34A, showing the piston-style drilling mud screen system a closed position mounted on the alternative skid **3400a**.

FIGS. 42A-1 and 42A-2 illustrate a cross-sectional view of an exemplary piston-style drilling mud screen system **4200** according to an embodiment of the invention, showing a reversed drilling mud screen **4240**.

As shown in FIGS. 33A-33C, 34A-34B, 42A-1 and 42A-2, the piston-style drilling mud screen system **3300**, **3400**, **4200** comprises a first subassembly **33000a**, **34000a**, **42000a**, a first body **3305a**, **3405a**, **4205a**, a union system **33102**, **42102** (discussed below), a second body **3305b**, **3405b**, **4205b** and a second subassembly **33000b**, **34000b**, **42000a**. The piston-style drilling mud screen system **3300**, **3400**, **4200** has a first subassembly **33000a**, **34000a**, **42000a** having a first end **33010a**, **34010a**, **42010a** and a second end **33015a**, **34015a**, **42015a**, a first inlet **33020a**, **34020a**, **42020a** of the first subassembly **33000a**, **34000a**, **42000a** and a first outlet **33025a**, **34025a** of the first subassembly **33000a**, **34000a**, **42000a**. The piston-style drilling mud screen system **3300**, **3400**, **4200** has a first body **3305a**, **3405a**, **4205a** having a first end **3310a**, **4210a** and a second end **3315a**, **4215a**, a first drilling mud inlet **3320a**, **4220a** of the first body **3305a**, **3405a**, **4205a** and a first drilling mud outlet **3325a**, **3425a**, **4225a** of the first body **3305a**, **3405a**, **4205a** (and a first drilling mud screen access port **3330a**, **3430a**, **4230a** of the first body **3305a**, **3405a**, **4205a**). The piston-style drilling mud screen system **3300**, **3400**, **4200** has a second body **3305b**, **3405b**, **4205b** having a first end **3310b**, **4210b** and a second end **3315b**, **4215b**, a second drilling mud inlet **3320b**, **4220b** of the second body **3305b**, **3405b**, **4205b** (and a second drilling mud screen access port **3330b**, **3430b**, **4230b** of the second body **3305b**, **3405b**, **4205b**) and a second drilling mud outlet **3325b**, **4225b** of the second body **3305b**, **3405b**, **4205b**. The piston-style drilling mud screen system **3300**, **3400**, **4200** has a second subassembly **33000b**, **34000b**, **42000b** having a first end **33010b**, **34010b**, **42010b** and a second end **33015b**, **34015b**, **42015b**,

a second inlet 33020b, 42020b of the second subassembly 33000b, 34000b, 42000b and a second outlet 33025b, 34025b, 42025b of the second subassembly 33000b, 34000b, 42000b.

In an embodiment, the second end 3315a, 4215a of the first body 3305a, 3405a, 4205a may be modified to reduce inside surface exit angle to transition a first inner diameter 3365a of the first drilling mud outlet 3325a, 4225a of the first body 3305a, 3405a, 4205a to a third inner diameter 33185c of a third body 33108c, 34108c, 42108c of a union system 33102, 34102, 42102, as discussed below. In an embodiment, the exit angle may be from about 10-degrees to about 90-degrees, and any range or value there between, with respect to the first centerline 3345a, 4245a of the first body 3305a, 3405a, 4205a. In an embodiment, the exit angle may be about 40-degrees. See e.g., FIGS. 33A-33C, 42A-1 & 42A-2.

In an embodiment, the first end 3310b, 4210b of the second body 3305b, 3405b, 4205b may be modified to reduce inside surface entry angle to transition the third inner diameter 33185c of a third body 33108c, 34108c, 42108c of a union system 33102, 34102, 42102 to a second inner diameter 3365b of the second drilling mud inlet 3320b, 4220b of the second body 3305b, 3405b, 4205b, as discussed below. In an embodiment, the entry angle may be from about 10-degrees to about 90-degrees, and any range or value there between, with respect to the second centerline 3345b, 4245b of the second body 3305b, 3405b, 4205b. In an embodiment, the entry angle may be about 30-degrees. See e.g., FIGS. 33A-33C, 42A-1 & 42A-2.

In an embodiment, the first drilling mud inlet 33020a, 34020a, 42020a of the first subassembly 33000a, 34000a, 42000a may be fluidly connected to, for example, an outlet of a drilling mud pump via a connection; and the second drilling mud outlet 33025b, 34025b, 42025b of the second subassembly 33000b, 34000b, 42000b may be fluidly connected to an inlet of a vibrator hose via a connection. Any suitable connection may be used for the first drilling mud inlet 33020a, 34020a, 42020a of the first subassembly 33000a, 34000a, 42000a and the second drilling mud outlet 33025b, 34025b, 42025b of the second subassembly 33000b, 34000b, 42000b. For example, suitable connections include, but are not limited to, pipe fittings and welds. Connections are well known in the art. In an embodiment, the first drilling mud inlet 33020a, 34020a, 42020a of the first subassembly 33000a, 34000a, 42000a may be fluidly connected to, for example, an outlet of a drilling mud pump via a weld; and the second drilling mud outlet 33025b, 34025b, 42025b of the second subassembly 33000b, 34000b, 42000b may be fluidly connected to an inlet of a vibrator hose via a weld.

In an embodiment, the first drilling mud inlet 3320a, 4220a of the first body 3305a, 3405a, 4205a may be fluidly connected to the first drilling mud outlet 33025a, 42025a of the first subassembly 33000a, 34000a, 42000a via a connection; and the second drilling mud outlet 3325b, 4225b of the second body 3305b, 3405b, 4205b may be fluidly connected to the second drilling mud inlet 33020b, 42020b of the second subassembly 33000b, 34000b, 42000b via a connection. Any suitable connection may be used for the first drilling mud inlet 3320a, 4220a of the first body 3305a, 3405a, 4205a and second drilling mud outlet 3325b, 4225b of the second body 3305b, 3405b, 4205b. For example, suitable connections include, but are not limited to, pipe fittings and other connections. In an embodiment, the first drilling mud inlet 3320a, 4220a of the first body 3305a, 3405a, 4205a may be fluidly connected to, for example,

first drilling mud outlet 33025a, 42025a of a first subassembly 33000a, 34000a, 42000a via a pipe fitting; and the second drilling mud outlet 3325b, 4225b of the second body 3305b, 3405b, 4205b may be fluidly connected to a second drilling mud inlet 33020b, 42020b of the second subassembly 33000b, 34000b, 42000b via a pipe fitting.

In an embodiment, the first drilling mud outlet 3325a, 4225a of the first body 3305a, 3405a, 4205a may be fluidly connected to the second drilling mud inlet 3320b, 4220b of the second body 3305b, 3405b, 4205b via a union. In an embodiment, the union may be a union system 33102, 34102, 42102. In an embodiment, the first body 3305a, 3405a, 4205a and/or the second body 3305b, 3405b, 4205b may be sealed with the union system 33102, 34102, 42102 via an O-ring. Any suitable O-ring may be used. For example, suitable O-rings include, but are not limited to, 300 Series O-rings. O-rings are well known in the art.

In an embodiment, the first drilling mud outlet 3325a, 4225a of the first body 3305a, 3405a, 4205a may be fluidly connected to a first inlet 33125a, 42125a of a first body 33108a, 34108a, 42108a of the union system 33102, 34102, 42102. In an embodiment, the first body 3305a, 3405a, 4205a may be sealed with the union system 33102, 34102, 42102 via an O-ring. Any suitable O-ring may be used. For example, suitable O-rings include, but are not limited to, 300 Series O-rings. O-rings are well known in the art.

In an embodiment, a first outlet 33125a, 42125a of the first body 33108a, 34108a, 42108a of the union system 33102, 34102, 42102 may be fluidly connected to a third inlet 33120c, 42120c of a third body 33108c, 34108c, 42108c of the union system 33102, 34102, 42102. In an embodiment, the first body 33108a, 34108a, 42108a of the union system 33102, 34102, 42102 may be sealed with the third body 33108c, 34108c, 42108c of the union system 33102, 34102, 42102 via an O-ring. Any suitable O-ring may be used. For example, suitable O-rings include, but are not limited to, 300 Series O-rings. O-rings are well known in the art.

In an embodiment, the second outlet 33125b, 42125b of the second body 33108b, 34108b, 42108b of the union system 33102, 34102, 42102 may be fluidly connected to the second drilling mud inlet 3320b, 4220b of the second body 3305b, 3405b, 4205b. In an embodiment, the second body 3305b, 3405b, 4205b may be sealed with the union system 33102, 34102, 42102 via an O-ring. Any suitable O-ring may be used. For example, suitable O-rings include, but are not limited to, 300 Series O-rings. O-rings are well known in the art.

In an embodiment, the first subassembly 33000a, 34000a, 42000a and the second subassembly 33000b, 34000b, 42000b of the drilling mud screen system 3300, 3400, 4200 may be constructed of any suitable material. For example, suitable materials include, but are not limited to, any alloy steel suitable for a drilling mud application. In an embodiment, the first subassembly 33000a, 34000a, 42000a and the second subassembly 33000b, 34000b, 42000b may be constructed of an AISI 4130/75k yield or equivalent material. In an embodiment, the inner surface of the first subassembly 33000a, 34000a, 42000a and the second subassembly 33000b, 34000b, 42000b may be unpainted. In an embodiment, the outer surface of the first subassembly 33000a, 34000a, 42000a and the second assembly 33000b, 34000b, 42000b may be painted.

In an embodiment, the first body 3305a, 3405a, 4205a and the second body 3305b, 3405b, 4205b of the drilling mud screen system 3300, 3400, 4200 may be constructed of any suitable material. For example, suitable materials

include, but are not limited to, any alloy steel suitable for a drilling mud application. In an embodiment, the first body **3305a, 3405a, 4205a** and the second body **3305b, 3405b, 4205b** may be constructed of an AISI 4130/75k yield or equivalent material. In an embodiment, the inner surface of the first body **3305a, 3405a, 4205a** and the second body **3305b, 3405b, 4205b** may be unpainted. In an embodiment, the outer surface of the first body **3305a, 3405a, 4205a** and the second body **3305b, 3405b, 4205b** may be painted.

In an embodiment, the drilling mud screen system **3300, 3400, 4200** has a length **3350, 4250**. The length **3350, 4250** may be any suitable length. In an embodiment, the length **3350, 4250** may be from about 20-inches to about 100-inches, and any range or value there between. In an embodiment, the length **3350, 4250** may be about 51-inches or about 52-inches.

In an embodiment, the drilling mud screen system **3300, 3400, 4200**, including a first subassembly **33000a, 34000a, 42000a** and a second subassembly **33000b, 34000b, 42000b**, has a length **33050, 42050**. The length **33050, 42050** may be any suitable length. In an embodiment, the length **33050, 42050** may be from about 20-inches to about 100-inches, and any range or value there between. In an embodiment, the length **33050, 42050** may be about 50-inches.

In an embodiment, the first subassembly **33000a, 34000a, 42000a** has a first centerline **33045a, 42045a** and a first length **33050a, 42050a**. In an embodiment, the first centerline **33045a, 42045a, 42045a** extends through the center of the first drilling mud screen inlet **33020a, 34020a, 42020a** of the first subassembly **33000a, 34000a, 42000a** to the first drilling mud outlet **33025a, 42025a** of the first subassembly **33000a, 34000a, 42000a** (and the first drilling mud screen inlet **3320a, 4220a** of the first body **3305a, 3405a, 4205a**). The first length **33050a, 42050a** of the first subassembly **33000a, 34000a, 42000a** may be any suitable length. In an embodiment, the first length **33050a, 42050a** of the first subassembly **33000a, 34000a, 42000a** may be from about 4-inches to about 10-inches, and any range or value there between. In an embodiment, the first length **33050a, 42050a** of the first subassembly **33000a, 34000a, 42000a** may be about 6-inches.

In an embodiment, the first drilling mud inlet **33020a, 34020a, 42020a** of the first subassembly **33000a, 34000a, 42000a** may have any suitable first inner diameter **33065a**; and the first drilling mud inlet **33020a, 34020a, 42020a** of the first subassembly **33000a, 34000a, 42000a** may have any suitable first outer diameter **33070a**. In an embodiment, the first inner diameter **33065a** of the first drilling mud inlet **33020a, 34020a, 42020a** may be from about 3-inches to about 5-inches, and any range or value there between. In an embodiment, the first inner diameter **33065a** of the first drilling mud inlet **33020a, 34020a, 42020a** may be about 4-inches.

In an embodiment, the first outer diameter **33070a** of the first drilling mud inlet **33020a, 34020a, 42020a** may be from about 4.5-inches to about 6.5-inches, and any range or value there between. In an embodiment, the first outer diameter **33070a** of the first drilling mud inlet **33020a, 34020a, 42020a** may be about 5.5-inches.

In an embodiment, the second subassembly **33000b, 34000b, 42000b** has a second centerline **33045b, 42045b** and a second length **33050b, 42050b**. In an embodiment, the second centerline **33045b, 42045b** extends through the center of the second drilling mud screen inlet **33020b, 42020b** of the second subassembly **33000b, 34000b, 42000b** (and the second drilling mud outlet **3325b, 4225b** of the second body **3305b, 3405b, 4205b**) to the second drilling mud outlet

33020b, 42020b of the second subassembly **33000b, 34000b, 42000b**. The second length **33050b, 42050b** of the second subassembly **33000b, 34000b, 42000b** may be any suitable length. In an embodiment, the second length **33050b, 42050b** of the second subassembly **33000b, 34000b, 42000b** may be from about 4-inches to about 10-inches, and any range or value there between. In an embodiment, the second length **33050b, 33050b** of the second subassembly **33000b, 34000b, 42000b** may be about 6-inches.

In an embodiment, the second drilling mud inlet **33020b, 42020b** of the second subassembly **33000b, 34000b, 42000b** may have any suitable second inner diameter **33065b**; and the second drilling mud inlet **33020b, 42020b** of the second subassembly **33000b, 34000b, 42000b** may have any suitable second outer diameter **33070b**. In an embodiment, the second inner diameter **33065b** of the second drilling mud inlet **33020b, 42020b** may be from about 3-inches to about 5-inches, and any range or value there between. In an embodiment, the second inner diameter **33065b** of the second drilling mud inlet **33020b, 42020b** may be about 4-inches.

In an embodiment, the second outer diameter **33070b** of the second drilling mud inlet **33020b, 42020b** may be from about 6-inches to about 10-inches, and any range or value there between. In an embodiment, the second outer diameter **33070b** of the second drilling mud inlet **33020b, 42020b** may be about 8-inches.

In an embodiment, the first body **3305a, 3405a, 4205a** has a first centerline **3345a, 4245a** and a first length **3350a, 4250a**. In an embodiment, the first centerline **3345a, 4245a** extends through the center of the first drilling mud screen inlet **3320a, 4220a** to the first drilling mud outlet **3325a, 4225a** (and the first drilling mud screen access port **3330a, 3430a, 4230a**). The first length **3350a, 4250a** of the first body **3305a, 3405a, 4205a** may be any suitable length. In an embodiment, the first length **3350a, 4250a** of the first body **3305a, 3405a, 4205a** may be from about 15-inches to about 60-inches, and any range or value there between. In an embodiment, the first length **3350a, 4250a** of the first body **3305a, 3405a, 4205a** may be about 18.5-inches.

In an embodiment, the first drilling mud inlet **3320a, 4220a** may have any suitable first inner diameter **3365a**; and the first drilling mud inlet **3320a, 4220a** may have any suitable first outer diameter **3370a**. In an embodiment, the first inner diameter **3365a** of the first drilling mud inlet **3320a, 4220a** may be from about 3-inches to about 5-inches, and any range or value there between. In an embodiment, the first inner diameter **3365a** of the first drilling mud inlet **3320a, 4220a** may be about 4-inches.

In an embodiment, the first outer diameter **3370a** of the first drilling mud inlet **3320a, 4220a** may be from about 4-inches to about 10-inches, and any range or value there between. In an embodiment, the first outer diameter **3370a** of the first drilling mud inlet **3320a, 4220a** may be about 6.5-inches.

In an embodiment, the first drilling mud outlet **3325a, 4225a** may have any suitable first inner diameter **3365a**; and the first drilling mud outlet **3325a, 4225a** may have any suitable first outer diameter **3370a**. In an embodiment, the first inner diameter **3365a** of the first drilling mud outlet **3325a, 4225a** may be from about 3-inches to about 5-inches, and any range or value there between. In an embodiment, the first inner diameter **3365a** of the first drilling mud outlet **3325a, 4225a** may be about 4-inches.

In an embodiment, the first outer diameter **3370a** of the first drilling mud outlet **3325a, 4225a** may be from about

4-inches to about 10-inches, and any range or value there between. In an embodiment, the first outer diameter 3370a of the first drilling mud outlet 3325a, 4225a may be about 6.5-inches.

In an embodiment, the second body 3305b, 3405b, 4205b has a second centerline 3345b, 4245b and a second length 3350b, 4250b. In an embodiment, the second centerline 3345b, 4245b extends through the center of the second drilling mud screen access port 3330b, 3430b, 4230b (and the second drilling mud inlet 3320b, 4220b) to the second drilling mud outlet 3325b, 4225b. The second length 3350b, 4250b of the second body 3305b, 3405b, 4205b may be any suitable length. In an embodiment, the second length 3350b, 4250b of the second body 3305b, 3405b, 4205b may be from about 15-inches to about 60-inches, and any range or value there between. In an embodiment, the second length 3350b, 4250b may be about 18-inches or about 19-inches.

In an embodiment, the second drilling mud inlet 3320b, 4220b may have any suitable second inner diameter 3365b; and the second drilling mud inlet 3320b, 4220b may have any suitable second outer diameter 3370b. In an embodiment, the second inner diameter 3365b of the second drilling mud inlet 3320b, 4220b may be from about 3-inches to about 5-inches, and any range or value there between. In an embodiment, the second inner diameter 3365b of the second drilling mud inlet 3320b, 4220b may be about 4-inches.

In an embodiment, the second outer diameter 3370b of the second drilling mud inlet 3320b, 4220b may be from about 4-inches to about 10-inches, and any range or value there between. In an embodiment, the second outer diameter 3370b of the second drilling mud inlet 3320b, 4220b may be about 6.5-inches.

In an embodiment, the second drilling mud outlet 3325b, 4225b may have any suitable second inner diameter 3365b; and the second drilling mud outlet 3325b, 4225b may have any suitable second outer diameter 3370b. In an embodiment, the second inner diameter 3365b of the second drilling mud outlet 3325b, 4225b may be from about 3-inches to about 5-inches, and any range or value there between. In an embodiment, the second inner diameter 3365b of the second drilling mud outlet 3325b, 4225b may be about 4-inches.

In an embodiment, the second outer diameter 3370b of the second drilling mud outlet 3325b, 4225b may be from about 4-inches to about 10-inches, and any range or value there between. In an embodiment, the second outer diameter 3370b of the second drilling mud outlet 3325b, 4225b may be about 6.5-inches.

Union System

The piston-style drilling mud screen system 3300, 3400, 4200 has a union system 33102, 34102, 42102. The union system 33102, 34102, 42102 has a first body 33108a, 34108a, 42108a of the union system 33102, 34102, 42102 having a first end 33108a, 34108a, 42108a and a second end 33108b, 34108b, 42108b, a second body 33108b, 34108b, 42108b of the union system 33102, 34102, 42102 having a first end 33112a, 42112a and a second end 33115a, and a third body 33108c, 34108c, 42108c of the union system 33102, 34102, 42102 having a first end 33112c and a second end 33115c.

In an embodiment, the second end 3315a, 4215a of the first body 3305a, 3405a, 4205a may be disposed through the first end 33112c, 42112c of the third body 33108c, 34108c, 42108c of the union system 33102, 34102, 42102 such that the second end 3315a, 4215a of the first body 33108a, 34108a, 42108a of the union system 33102, 34102, 42102 is disposed between the second end 3315a, 4215a of the first body 3305a, 3405a, 4205a and the first end 33112c, 42112c

of the third body 33108c, 34108c, 42108c of the union system 33102, 34102, 42102. See e.g., FIGS. 33A-33C & 42A-42B.

In an embodiment, the union system 33102, 34102, 42102 may have a first union 33102a, 34102a, 42102a and a second union 33102b, 34102b, 42102b.

In an embodiment, the first union 33102a, 34102a, 42102a may comprise the first body 33108a, 34108a, 42108a of the union system 33102, 34102, 42102 and a portion of the first end 33112c, 42112c of the third body 33108c, 34108c, 42108c of the union system 33102, 34102, 42102.

In an embodiment, the second union 33102b, 34102b, 42102b may comprise the second body 33108b, 34108b, 42108b and a portion of the second end 33115c, 42115c of the third body 33108c, 34108c, 42108c of the union system 33102, 34102, 42102.

In an embodiment, the second end 3315a, 4215a of the first body 3305a, 3405a, 4205a and the first end 33112a, 42112a and/or the second end 33115a, 42115a of the first body 33108a, 34108a, 42108a of the union system 33102, 34102, 42102 may be sealed via an O-ring. Any suitable O-ring may be used. For example, suitable O-rings include, but are not limited to, 300 Series O-rings. O-rings are well known in the art.

In an embodiment, the first end 3310b, 4210b of the second body 3305b, 3405b, 4205b may be disposed through the second end 33115c, 42115c of the third body 33108c, 34108c, 42108c of the union system 33102, 34102, 42102 such that the first end 33112b, 42112b of the second body 33108b, 34108b, 42108b of the union system 33102, 34102, 42102 is disposed between the second end 33115c, 42115c of the third body 33108c, 34108c, 42108c of the union system 33102, 34102, 42102 and the first end 3310b, 4210b of the second body 3305b, 3405b, 4205b. See e.g., FIGS. 33A-33C & 42A-42B.

In an embodiment, the first end 3310b, 4210b of the second body 3305b, 3405b, 4205b and the first end 33112b, 42112b and/or the second end 33115b, 42115b of the second body 33108b, 34108b, 42108b of the union system 33102, 34102, 42102 may be sealed via an O-ring. Any suitable O-ring may be used. For example, suitable O-rings include, but are not limited to, 300 Series O-rings. O-rings are well known in the art.

In an embodiment, the second end 33115a, 42115a of the first body 33108a, 34108a, 42108a and the first end 33112c, 42112c of the third body 33108c, 34108c, 42108c of the union system 33102, 34102, 42102 may be attached by a connection. Any suitable connection may be used for the second end 33115a, 42115a of the first body 33105a, 34105a, 42105a and the first end 33112c, 42112c of the third body 33108c, 34108c, 42108c of the union system 33102, 34102, 42102. For example, suitable connections include, but are not limited to, pipe fittings and threads. Connections are well known in the art. In an embodiment, the first end 33112c, 42112c of the third body 33108c, 34108c, 42108c of the union system 33102, 34102, 42102 may be threaded into the second end 33115a, 42115a of the first body 33108a, 34108a, 42108a of the union system 33102, 34102, 42102.

In an embodiment, the second end 33115a, 42115a of the first body 33108a, 34108a, 42108a of the union system 33102, 34102, 42102 may be threaded into the first end 33112c, 42112c of the third body 33108c, 34108c, 42108c of the union system 33102, 34102, 42102.

In an embodiment, the second end 33115a, 42115a of the first body 33108a, 34108a, 42108a of the union system 33102, 34102, 42102 and the first end 33112c, 42112c of the

third body 33108c, 34108c, 42108c of the union system 33102, 34102, 42102 may be sealed via an O-ring. Any suitable O-ring may be used. For example, suitable O-rings include, but are not limited to, 300 Series O-rings. O-rings are well known in the art.

In an embodiment, the first body 33108a, 34108a, 42108a, the second body 33108b, 34108b, 42108b, and the third body 33108c, 34108c, 42108c of the union system 33102, 34102, 42102 may be constructed of any suitable material. For example, suitable materials include, but are not limited to, any alloy steel suitable for a drilling mud application. In an embodiment, the first body 33108a, 34108a, 42108a, the second body 33108b, 34108b, 42108b and the third body 33108c, 34108c, 42108c may be constructed of an AISI 4130/75k yield or equivalent material. In an embodiment, the inner surface of the first body 33108a, 34108a, 42108a, the second body 33108b, 34108b, 42108b and the third body 33108c, 34108c, 42108c may be unpainted. In an embodiment, the outer surface of the first body 33108a, 34108a, 42108a, the second body 33108b, 34108b, 42108b and the third body 33108c, 34108c, 42108c may be painted.

In an embodiment, the union system 33102, 34102, 42102 has a length 33150, 42150. The length 33150, 42150 may be any suitable length. In an embodiment, the length 33150, 42150 may be from about 10-inches to about 40-inches, and any range or value there between. In an embodiment, the length 33150, 42150 may be about 24-inches or about 25-inches.

In an embodiment, the first body 33108a, 34108a, 42108a has a first centerline 33145a, 42145a and a first length 33150a, 42150a. In an embodiment, the first centerline 33145a, 42145a extends through the center of the first inlet 33120a, 42120a to the first outlet 33125a, 42125a. The first length 33150a, 42150a of the first body 33108a, 34108a, 42108a may be any suitable length. In an embodiment, the first length 33150a, 42150a of the first body 33108a, 34108a, 42108a, 42108a may be from about 4-inches to about 15-inches, and any range or value there between. In an embodiment, the first length 33150a, 42150a may be about 5-inches or about 6-inches.

In an embodiment, the first inlet 33120a, 42120a of the first body 33108a, 34108a, 42108a may have any suitable first inner diameter 33165a; and the first inlet 33120a, 42120a of the first body 33108a, 34108a, 42108a may have any suitable first outer diameter 33170a. In an embodiment, the first inner diameter 33165a of the first inlet 33120a, 34120a, 42120a may be from about 3-inches to about 5-inches, and any range or value there between. In an embodiment, the first inner diameter 33165a of the first inlet 33120a, 42120a may be about 4-inches.

In an embodiment, the first outer diameter 33170a of the first inlet 33120a, 34120a, 42120a may be from about 6-inches to about 12-inches, and any range or value there between. In an embodiment, the first outer diameter 33170a of the first inlet 33120a, 34120a, 42120a may be about 9.5-inches.

In an embodiment, the first body 33108a, 34108a, 42108a may have any suitable first inner diameter 33185a; and the first body 33108a, 34108a, 42108a may have any suitable first outer diameter 33190a. In an embodiment, the first inner diameter 33185a of the first body 33108a, 34108a, 42108a may be from about 6-inches to about 12-inches, and any range or value there between. In an embodiment, the first inner diameter 33185a of the first body 33108a, 34108a, 42108a may be about 9.5-inches.

In an embodiment, the first outer diameter 33190a of the first body 33108a, 34108a, 42108a may be from about 6-inches to about 12-inches, and any range or value there between. In an embodiment, the first outer diameter 33090a of the first body 33108a, 34108a, 42108a may be about 8.5-inches.

In an embodiment, the first outlet 33125a, 42125a of the first body 33108a, 34108a, 42108a may have any suitable first inner diameter 33200a; and the first outlet 33125a, 42125a of the first body 33108a, 34108a, 42108a may have any suitable first outer diameter 33195a. In an embodiment, the first inner diameter 33200a of the first outlet 33125a, 42125a may be from about 4-inches to about 10-inches (e.g., outer diameter of first body 3305a, 3405a, 4205a), and any range or value there between. In an embodiment, the first inner diameter 33200a of the first outlet 33125a, 42125a may be about 8.5-inches.

In an embodiment, the second body 33108b, 34108b, 42108b has a second centerline 33145b, 42145b and a second length 33150b, 42150b. In an embodiment, the second centerline 33145b, 42145b extends through the center of the second inlet 33120b, 42120b to the second outlet 33125b, 42125b. The second length 33150b, 42150b of the second body 33108b, 34108b, 42108b may be any suitable length. In an embodiment, the second length 33150b, 42150b of the second body 33108b, 34108b, 42108b may be from about 4-inches to about 12-inches, and any range or value there between. In an embodiment, the second length 33150b, 42150b may be about 5-inches or about 6-inches.

In an embodiment, the second inlet 33120b, 42120b of the second body 33108b, 34108b, 42108b may have any suitable second inner diameter 33200b; and the second inlet 33120b, 42120b of the second body 33108b, 34108b, 42108b may have any suitable second outer diameter 33195b. In an embodiment, the second inner diameter 33200b of the second inlet 33120b, 42120b may be from about 4-inches to about 10-inches (e.g., outer diameter of second body 3305b, 3405b, 4205b), and any range or value there between. In an embodiment, the second inner diameter 33200a of the second inlet 33120b, 42120b may be about 8.5-inches.

In an embodiment, the second body 33108b, 34108b, 42108b may have any suitable second inner diameter 33185b; and the second body 33108b, 34108b, 42108b may have any suitable second outer diameter 33190b. In an embodiment, the second inner diameter 33185b of the second body 33108b may be from about 6-inches to about 12-inches, and any range or value there between. In an embodiment, the second inner diameter 33185b of the second body 33108b may be about 9.5-inches.

In an embodiment, the second outer diameter 33190b of the second body 33108b, 34108b, 42108b may be from about 6-inches to about 12-inches, and any range or value there between. In an embodiment, the second outer diameter 33190b of the second body 33108b, 34108b, 42108b may be about 9.5-inches.

In an embodiment, the second outlet 33125b, 42125b of the second body 33108b, 34108b, 42108b may have any suitable second inner diameter 33165b; and the second outlet 33125b, 42125b of the second body 33108b, 34108b, 42108b may have any suitable second outer diameter 33170b. In an embodiment, the second inner diameter 33165b of the second outlet 33125b, 42125b may be from about 4-inches to about 6-inches, and any range or value there between. In an embodiment, the second inner diameter 33165b of the second outlet 33125b, 42125b may be about 5-inches.

In an embodiment, the second outer diameter **33070b** of the second outlet **33125b**, **42125b** may be from about 6-inches to about 12-inches, and any range or value there between. In an embodiment, the second outer diameter **33070b** of the second outlet **33125b**, **42125b** may be about 9.5-inches.

In an embodiment, the third body **33108c**, **34108c**, **42108c** has a third centerline **33145c**, **42145c** and a third length **33150c**, **42150c**. In an embodiment, the third centerline **33145c** extends through the center of the third inlet **33120c**, **42120c** to the third outlet **33125c**, **42125c**. The third length **33150c**, **42150c** of the third body **33108c**, **34108c**, **42108c** may be any suitable length. In an embodiment, the third length **33150c**, **42150c** of the third body **33108c**, **34108c**, **42108c** may be from about 10-inches to about 40-inches, and any range or value there between. In an embodiment, the third length **33150c**, **42150c** may be about 21.5-inches.

In an embodiment, the third inlet **33120c**, **42120c** of the third body **33108c**, **34108c**, **42108c** may have any suitable third inner diameter **33200c**; and the third inlet **33120c**, **42120c** of the third body **33108c**, **34108c**, **42108c** may have any suitable third outer diameter **33195c**. In an embodiment, the third inner diameter **33200c** of the third inlet **33120c**, **42120c** may be from about 6-inches to about 12-inches, and any range or value there between. In an embodiment, the third inner diameter **33200c** of the third inlet **33120c**, **42120c** may be about 8.5-inches.

In an embodiment, the third body **33108c**, **34108c**, **42108c** may have any suitable third inner diameter **33185c**; and the third body **33108c**, **34108c**, **42108c** may have any suitable third outer diameter **33190c**. In an embodiment, the third inner diameter **33185c** of the third body **33108c**, **34108c**, **42108c** may be from about 6-inches to about 15-inches, and any range or value there between. In an embodiment, the third inner diameter **33185c** of the third body **33108c**, **34108c**, **42108c** may be about 10.5-inches.

In an embodiment, the third outer diameter **33190c** of the third body **33108c**, **34108c**, **42108c** may be from about 6-inches to about 15-inches, and any range or value there between. In an embodiment, the third outer diameter **33190c** of the third body **33108c**, **34108c**, **42108c** may be about 10.5-inches.

In an embodiment, the third outlet **33125c**, **42125c** of the third body **33108c**, **34108c**, **42108c** may have any suitable third inner diameter **33165c**; and the third outlet **33125c**, **42125c** of the third body **33108c**, **34108c**, **42108c** may have any suitable third outer diameter **33170c**. In an embodiment, the third inner diameter **33165c** of the third outlet **33125c**, **42125c** may be from about 6-inches to about 12-inches, and any range or value there between. In an embodiment, the third inner diameter **33165c** of the third outlet **33125c**, **42125c** may be about 8.5-inches.

In an embodiment, the third outer diameter **33170c** of the third outlet **33125c**, **42125c** may be from about 6-inches to about 15-inches, and any range or value there between. In an embodiment, the third outer diameter **33170c** of the third outlet **33125c**, **42125c** may be about 10.5-inches.

Skid

As shown in FIGS. 30A-30E, 30G and 31, the piston-style drilling mud screen system **3000** may be mounted on a skid **3000a**. The skid **3000a** has a first support **3000b**, a second support **3000c**, a third support **3000d** and a base **3000e**.

In an embodiment, an upper end of the first support **3000b** may be mechanically coupled to a lower surface of the first subassembly **30000a** via a connection and/or a coupling; and the lower end of the first support **3000b** may be mechani-

cally coupled to an upper surface of the base **3000d** via a connection and/or a coupling.

In an embodiment, the first support **3000b** may be stationary when the third support **3000d** is pivotable and/or rotatable, raisable and/or lowerable, and any combination thereof.

In an embodiment, the first support **3000b** may be pivotable and/or rotatable. In an embodiment, an upper end of the first support **3000b** may be pivotable and/or rotatable. In an embodiment, a lower end of the first support **3000b** may be rotatable.

In an embodiment, the first support **3000b** may be raisable and/or lowerable. In an embodiment, an upper end of the first support **3000b** may be raisable and/or lowerable. In an embodiment, a lower end of the first support **3000b** may be raisable and/or lowerable.

Any suitable connection may be used for the first support **3000b**. For example, suitable connections include, but are not limited to, bands, clamps, fittings and welds.

In an embodiment, an upper end of the first support **3000b** may be attached to an outer surface of the first subassembly **30000a** by a connection. For example, suitable connections include, but are not limited to, bands, clamps, fittings and welds. In an embodiment, an upper end of the first support **3000b** may be attached to an outer surface of the first subassembly **30000a** by a band or a clamp.

In an embodiment, the lower end of the first support **3000b** may be attached to the upper surface of the skid **3000a** (e.g., base **3000e**) by a connection. For example, suitable connections include, but are not limited to, bands, clamps, fittings and welds. In an embodiment, the lower end of the first support **3000b** may be attached to the upper surface of the skid **3000a** (e.g., base **3000e**) by a connection. In an embodiment, the lower end of the first support **3000b** may be attached to the upper surface of the skid **3000a** (e.g., base **3000e**) by fittings or welds.

Any suitable coupling may be used for the first support **3000b**. For example, suitable couplings include, but are not limited to bearings, hinges, pivots, sockets, and combinations thereof. In an embodiment, the coupling for the first support **3000b** may be a bearing. In an embodiment, the coupling for the first support **3000b** may be a box channel with a pivot pin.

In an embodiment, the first support **3000b** may have a coupling at or near an upper end. For example, suitable couplings include, but are not limited to bearings, hinges, pivots, sockets, and combinations thereof. In an embodiment, the first support **3000b** may have a bearing or a socket at or near an upper end. In an embodiment, the first support **3000b** may have a hinge or a pivot at or near an upper end.

In an embodiment, the first support **3000b** may have a coupling at or near a lower end. For example, suitable couplings include, but are not limited to bearings, hinges, pivots, sockets, and combinations thereof. In an embodiment, the first support **3000b** may have a bearing or a socket at or near a lower end. In an embodiment, the first support **3000b** may have a hinge or a pivot at or near a lower end.

In an embodiment, the first support **3000b** may pivot and/or rotate automatically and/or manually. In an embodiment, the first support **3000b** may pivot and/or rotate electro-mechanically, hydraulically, mechanically (e.g., geared) or pneumatically. In an embodiment, the first support **3000b** may pivot and/or rotate manually.

Any suitable extension may be used for the first support **3000b**. For example, suitable extensions include, but are not limited to articulated arms, extendable pistons, telescoping pipes, and combinations thereof. In an embodiment, the

extension for the first support **3000b** may be an extendable piston. In an embodiment, the extension for the first support **3000b** may be a telescoping pipe with a clevis pin.

In an embodiment, the first support **3000b** may have an extension at or near an upper end. For example, suitable extensions include, but are not limited to articulated arms, extendable pistons, telescoping pipes, and combinations thereof. In an embodiment, the first support **3000b** may have an extendable arm at or near an upper end. In an embodiment, the first support **3000b** may have a telescoping pipe with a clevis pin at or near an upper end.

In an embodiment, the first support **3000b** may have an extension at or near a lower end. For example, suitable extensions include, but are not limited to articulated arms, extendable pistons, telescoping pipes, and combinations thereof. In an embodiment, the first support **3000b** may have an extendable piston at or near a lower end. In an embodiment, the first support **3000b** may have a telescoping pipe with a clevis pin at or near a lower end.

In an embodiment, the first support **3000b** may raise and/or lower automatically and/or manually. In an embodiment, the first support **3000b** may raise and/or lower electro-mechanically, hydraulically, mechanically (e.g., geared) or pneumatically. In an embodiment, the first support **3000b** may raise and/or lower manually.

In an embodiment, an upper end of the second stationary support **3000c** may be mechanically coupled to a lower surface of the second subassembly **30000b**; and the lower end of the second stationary support **3000c** may be mechanically coupled to an upper surface of the base **3000e**.

In an embodiment, the second support **3000c** may be stationary when the third support **3000d** is pivotable and/or rotatable, raisable and/or lowerable, and any combination thereof.

In an embodiment, the second support **3000c** may be pivotable and/or rotatable. In an embodiment, an upper end of the second support **3000c** may be pivotable and/or rotatable. In an embodiment, a lower end of the second support **3000c** may be rotatable.

In an embodiment, the second support **3000c** may be raisable and/or lowerable. In an embodiment, an upper end of the second support **3000c** may be raisable and/or lowerable. In an embodiment, a lower end of the second support **3000c** may be raisable and/or lowerable.

Any suitable connection may be used for the second support **3000c**. For example, suitable connections include, but are not limited to, fittings and welds. Connections are well known in the art.

In an embodiment, an upper end of the second support **3000c** may be attached to an outer surface of the second subassembly **30000b** by a connection. For example, suitable connections include, but are not limited to, bands, clamps, fittings and welds. In an embodiment, an upper end of the second support **3000c** may be attached to an outer surface of the second subassembly **30000b** by a band or a clamp.

In an embodiment, the lower end of the second support **3000c** may be attached to the upper surface of the skid **3000a** (e.g., base **3000e**) by a connection. For example, suitable connections include, but are not limited to, bands, clamps, fittings and welds. In an embodiment, the lower end of the second support **3000c** may be attached to the upper surface of the skid **3000a** (e.g., base **3000e**) by a connection. In an embodiment, the lower end of the second support **3000c** may be attached to the upper surface of the skid **3000a** (e.g., base **3000e**) by fittings or welds.

Any suitable coupling may be used for the second support **3000c**. For example, suitable couplings include, but are not

limited to bearings, hinges, pivots, sockets, and combinations thereof. In an embodiment, the coupling for the second support **3000c** may be a bearing. In an embodiment, the coupling for the second support **3000c** may be a box channel with a pivot pin.

In an embodiment, the second support **3000c** may have a coupling at or near an upper end. For example, suitable couplings include, but are not limited to bearings, hinges, pivots, sockets, and combinations thereof. In an embodiment, the second support **3000c** may have a bearing or a socket at or near an upper end. In an embodiment, the second support **3000c** may have a hinge or a pivot at or near an upper end.

In an embodiment, the second support **3000c** may have a coupling at or near a lower end. For example, suitable couplings include, but are not limited to bearings, hinges, pivots, sockets, and combinations thereof. In an embodiment, the second support **3000c** may have a bearing or a socket at or near a lower end. In an embodiment, the second support **3000c** may have a hinge or a pivot at or near a lower end.

In an embodiment, the second support **3000c** may pivot and/or rotate automatically and/or manually. In an embodiment, the second support **3000c** may pivot and/or rotate electro-mechanically, hydraulically, mechanically (e.g., geared) or pneumatically. In an embodiment, the second support **3000c** may pivot and/or rotate manually.

Any suitable extension may be used for the second support **3000c**. For example, suitable extensions include, but are not limited to articulated arms, extendable pistons, telescoping pipes, and combinations thereof. In an embodiment, the extension for the second support **3000c** may be an extendable piston. In an embodiment, the coupling for the second support **3000c** may be a telescoping pipe with a clevis pin.

In an embodiment, the second support **3000c** may have an extension at or near an upper end. For example, suitable extensions include, but are not limited to articulated arms, extendable pistons, telescoping pipes, and combinations thereof. In an embodiment, the second support **3000c** may have an extendable arm at or near an upper end. In an embodiment, the second support **3000c** may have a telescoping pipe with a clevis pin at or near an upper end.

In an embodiment, the second support **3000c** may have an extension at or near a lower end. For example, suitable extensions include, but are not limited to articulated arms, extendable pistons, telescoping pipes, and combinations thereof. In an embodiment, the second support **3000c** may have an extendable piston at or near a lower end. In an embodiment, the second support **3000c** may have a telescoping pipe with a clevis pin at or near a lower end.

In an embodiment, the second support **3000c** may raise and/or lower automatically and/or manually. In an embodiment, the second support **3000c** may raise and/or lower electro-mechanically, hydraulically, mechanically (e.g., geared) or pneumatically. In an embodiment, the second support **3000c** may raise and/or lower manually.

In an embodiment, an upper end of the third support **3000d** may be mechanically coupled to a lower surface of the lock system **30100** (e.g., a first body **30105a** of the lock system **30100**); and the lower end of the third support **3000d** may be mechanically coupled to an upper surface of the base **3000e**.

In an embodiment, the third support **3000d** may be stationary when the first support **3000b** and/or the second support **3000c** are pivotable and/or rotatable, raisable and/or lowerable, and any combination thereof.

In an embodiment, the third support **3000d** may be pivotable and/or rotatable. In an embodiment, an upper end of the third support **3000d** may be pivotable and/or rotatable. In an embodiment, the lower end of the third support **3000d** may be rotatable or stationary.

In an embodiment, the third support **3000d** may be raisable and/or lowerable. In an embodiment, an upper end of the third support **3000d** may be raisable and/or lowerable. In an embodiment, a lower end of the third support **3000d** may be raisable and/or lowerable.

Any suitable connection may be used for the third support **3000d**. For example, suitable connections include, but are not limited to, fittings and welds. Connections are well known in the art.

In an embodiment, an upper end of the third support **3000d** may be attached to an outer surface of the lock system **30100** by a connection. For example, suitable connections include, but are not limited to, bands, clamps, fittings and welds. In an embodiment, an upper end of the third support **3000d** may be attached to an outer surface of the lock system **30100** by a band or a clamp.

In an embodiment, the lower end of the third support **3000d** may be attached to the upper surface of the skid **3000a** (e.g., base **3000e**) by a connection. For example, suitable connections include, but are not limited to, bands, clamps, fittings and welds. In an embodiment, the lower end of the third support **3000d** may be attached to the upper surface of the skid **3000a** (e.g., base **3000e**) by a connection. In an embodiment, the lower end of the third support **3000d** may be attached to the upper surface of the skid **3000a** (e.g., base **3000e**) by fittings or welds.

Any suitable coupling may be used for the third support **3000d**. For example, suitable couplings include, but are not limited to bearings, hinges, pivots, sockets, and combinations thereof. In an embodiment, the coupling for the third support **3000d** may be a bearing. In an embodiment, the coupling for the third support **3000d** may be a box channel with a pivot pin.

In an embodiment, the third support **3000d** may have a coupling at or near an upper end. For example, suitable couplings include, but are not limited to bearings, hinges, pivots, sockets, and combinations thereof. In an embodiment, the third support **3000d** may have a bearing or a socket at or near an upper end. In an embodiment, the third support **3000d** may have a hinge or a pivot at or near an upper end.

In an embodiment, the third support **3000d** may have a coupling at or near a lower end. For example, suitable couplings include, but are not limited to bearings, hinges, pivots, sockets, and combinations thereof. In an embodiment, the third support **3000d** may have a bearing or a socket at or near a lower end. In an embodiment, the third support **3000d** may have a hinge or a pivot at or near a lower end.

In an embodiment, the third support **3000d** may pivot and/or rotate automatically and/or manually. In an embodiment, the third support **3000d** may pivot and/or rotate electro-mechanically, hydraulically, mechanically (e.g., geared) or pneumatically. In an embodiment, the third support **3000d** may pivot and/or rotate manually.

Any suitable extension may be used for the third support **3000d**. For example, suitable extensions include, but are not limited to articulated arms, extendable pistons, telescoping pipes, and combinations thereof. In an embodiment, the extension for the third support **3000d** may be an extendable piston. In an embodiment, the extension for the third support **3000d** may be a telescoping pipe with a clevis pin.

In an embodiment, the third support **3000d** may have an extension at or near an upper end. For example, suitable

extensions include, but are not limited to articulated arms, extendable pistons, telescoping pipes, and combinations thereof. In an embodiment, the third support **3000d** may have an extendable arm at or near an upper end. In an embodiment, the third support **3000d** may have a telescoping pipe with a clevis pin at or near an upper end.

In an embodiment, the third support **3000d** may have an extension at or near a lower end. For example, suitable extensions include, but are not limited to articulated arms, extendable pistons, telescoping pipes, and combinations thereof. In an embodiment, the third support **3000d** may have an extendable piston at or near a lower end. In an embodiment, the third support **3000d** may have a telescoping pipe with a clevis pin at or near a lower end.

In an embodiment, the third support **3000d** may raise and/or lower automatically and/or manually. In an embodiment, the third support **3000d** may raise and/or lower electro-mechanically, hydraulically, mechanically (e.g., geared) or pneumatically. In an embodiment, the third support **3000d** may raise and/or lower manually.

In an embodiment, the first support **3000b**, the second support **3000c** and/or the third support **3000d** of the skid **3000a** of the drilling mud screen system **3000** may be constructed of any suitable material. For example, suitable materials include, but are not limited to, any alloy steel suitable for a drilling mud application. In an embodiment, the first support **3000b**, the second support **3000c**, and/or the third support **3000d** of the skid **3000a** may be constructed of an alloy steel or equivalent material. See e.g., FIGS. 30A-30E. In an embodiment, the first support **3000b**, the second support **3000c**, and/or the third support **3000d** of the skid **3000a** may be constructed of a 304 stainless steel material. In an embodiment, the first support **3000b**, the second support **3000c**, and/or the third support **3000d** of the skid **3000a** may be unpainted. In an embodiment, the first support **3000b**, the second support **3000c**, and/or the third support **3000d** of the skid **3000a** may be painted.

In an embodiment, the base **3000e** of the skid **3000a** of the drilling mud screen system **3000** may be constructed of any suitable material. For example, suitable materials include, but are not limited to, a concrete, a polymer, and any alloy steel suitable for a drilling mud application. In an embodiment, the base **3000e** may be constructed of a concrete. In an embodiment, the base **3000e** may be constructed of a polymer. In an embodiment, the base **3000e** of the skid **3000a** may be constructed of an alloy steel or equivalent material. See e.g., FIGS. 30A-30E. In an embodiment, the base **3000e** of the skid **3000a** may be constructed of a 304 stainless steel material. In an embodiment, the base **3000e** of the skid **3000a** may be unpainted. In an embodiment, the base **3000e** of the skid **3000a** may be painted.

Alternative Skid

As shown in FIGS. 33A-33C, 34A-34B, 42A-1 and 42A-2, the piston-style drilling mud screen system **3300**, **3400**, **4200** may be mounted on a skid **3300a**, **3400a**, **4200a**. The skid **3300a**, **3400a**, **4200a** has a first support **3300b**, **3400b**, **4200b**, a second support **3300c**, **3400c**, **4200c**, a third support **3300d**, **3400d**, **4200d** and a base or frame **3300e**, **3400e**, **4200e**.

In an embodiment, an upper end of the first support **3300b**, **3400b**, **4200b** may be mechanically coupled to a lower surface of the first subassembly **33000a**, **34000a**, **42000a** via a connection and/or a coupling; and the lower end of the first support **3300b**, **3400b**, **4200b** may be mechanically coupled to an upper surface of the base or frame **3300e**, **3400e**, **4200e** via a connection and/or a coupling.

In an embodiment, the first support **3300b, 3400b, 4200b** may be stationary when the third support **3300d, 3400d, 4200d** is pivotable and/or rotatable, raisable and/or lowerable, and any combination thereof.

In an embodiment, the first support **3300b, 3400b, 4200b** may be pivotable and/or rotatable. In an embodiment, an upper end of the first support **3300b, 3400b, 4200b** may be pivotable and/or rotatable. In an embodiment, a lower end of the first support **3300b, 3400b, 4200b** may be rotatable.

In an embodiment, the first support **3300b, 3400b, 4200b** may be raisable and/or lowerable. In an embodiment, an upper end of the first support **3300b, 3400b, 4200b** may be raisable and/or lowerable. In an embodiment, a lower end of the first support **3300b, 3400b, 4200b** may be raisable and/or lowerable.

Any suitable connection may be used for the first support **3300b, 3400b, 4200b**. For example, suitable connections include, but are not limited to, bands, clamps, fittings and welds.

In an embodiment, an upper end of the first support **3300b, 3400b, 4200b** may be attached to an outer surface of the first subassembly **33000a, 34000a, 42000a** by a connection. For example, suitable connections include, but are not limited to, bands, clamps, fittings, saddles and welds. In an embodiment, an upper end of the first support **3300b, 3400b, 4200b** may be attached to an outer surface of the first subassembly **33000a, 34000a, 42000a** by a band, a clamp and/or a saddle.

In an embodiment, the lower end of the first support **3300b, 3400b, 4200b** may be attached to the upper surface of the skid **3300a, 3400a, 4200a** (base or frame **3300e, 3400e, 4200e**) by a connection. For example, suitable connections include, but are not limited to, bands, clamps, fittings and welds. In an embodiment, the lower end of the first support **3300b, 3400b, 4200b** may be attached to the upper surface of the skid **3300a, 3400a, 4200a** (base or frame **3300e, 3400e, 4200e**) by a connection. In an embodiment, the lower end of the first support **3300b, 3400b, 4200b** may be attached to the upper surface of the skid **3300a, 3400a, 4200a** (base or frame **3300e, 3400e, 4200e**) by fittings or welds.

Any suitable coupling may be used for the first support **3300b, 3400b, 4200b**. For example, suitable couplings include, but are not limited to bearings, hinges, pivots, sockets, and combinations thereof. In an embodiment, the coupling for the first support **3300b, 3400b, 4200b** may be a bearing. In an embodiment, the coupling for the first support **3300b, 3400b, 4200b** may be a box channel with a pivot pin.

In an embodiment, the first support **3300b, 3400b, 4200b** may have a coupling at or near an upper end. For example, suitable couplings include, but are not limited to bearings, hinges, pivots, sockets, and combinations thereof. In an embodiment, the first support **3300b, 3400b, 4200b** may have a bearing or a socket at or near an upper end. In an embodiment, the first support **3300b, 3400b, 4200b** may have a hinge or a pivot at or near an upper end.

In an embodiment, the first support **3300b, 3400b, 4200b** may have a coupling at or near a lower end. For example, suitable couplings include, but are not limited to bearings, hinges, pivots, sockets, and combinations thereof. In an embodiment, the first support **3300b, 3400b, 4200b** may have a bearing or a socket at or near a lower end. In an embodiment, the first support **3300b, 3400b, 4200b** may have a hinge or a pivot at or near a lower end.

In an embodiment, the first support **3300b, 3400b, 4200b** may pivot and/or rotate automatically and/or manually. In an

embodiment, the first support **3300b, 3400b, 4200b** may pivot and/or rotate electro-mechanically, hydraulically, mechanically (e.g., geared) or pneumatically. In an embodiment, the first support **3300b, 3400b, 4200b** may pivot and/or rotate manually.

Any suitable extension may be used for the first support **3300b, 3400b, 4200b**. For example, suitable extensions include, but are not limited to articulated arms, extendable pistons, telescoping pipes, and combinations thereof. In an embodiment, the extension for the first support **3300b, 3400b, 4200b** may be an extendable piston. In an embodiment, the extension for the first support **3300b, 3400b, 4200b** may be a telescoping pipe with a clevis pin.

In an embodiment, the first support **3300b, 3400b, 4200b** may have an extension at or near an upper end. For example, suitable extensions include, but are not limited to articulated arms, extendable pistons, telescoping pipes, and combinations thereof. In an embodiment, the first support **3300b, 3400b, 4200b** may have an extendable arm at or near an upper end. In an embodiment, the first support **3300b, 3400b, 4200b** may have a telescoping pipe with a clevis pin at or near an upper end.

In an embodiment, the first support **3300b, 3400b, 4200b** may have an extension at or near a lower end. For example, suitable extensions include, but are not limited to articulated arms, extendable pistons, telescoping pipes, and combinations thereof. In an embodiment, the first support **3300b, 3400b, 4200b** may have an extendable piston at or near a lower end. In an embodiment, the first support **3300b, 3400b, 4200b** may have a telescoping pipe with a clevis pin at or near a lower end.

In an embodiment, the first support **3300b, 3400b, 4200b** may raise and/or lower automatically and/or manually. In an embodiment, the first support **3300b, 3400b, 4200b** may raise and/or lower electro-mechanically, hydraulically, mechanically (e.g., geared) or pneumatically. In an embodiment, the first support **3300b, 3400b, 4200b** may raise and/or lower manually.

In an embodiment, an upper end of the second stationary support **3300c, 3400c, 4200c** may be mechanically coupled to a lower surface of the second subassembly **33000b, 34000b, 42000b**; and the lower end of the second stationary support **3300c, 3400c, 4200c** may be mechanically coupled to an upper surface of the base or frame **3300e, 3400e, 4200e**.

In an embodiment, the second support **3300c, 3400c, 4200c** may be stationary when the third support **3300d, 3400d, 4200d** is pivotable and/or rotatable, raisable and/or lowerable, and any combination thereof.

In an embodiment, the second support **3300c, 3400c, 4200c** may be pivotable and/or rotatable. In an embodiment, an upper end of the second support **3300c, 3400c, 4200c** may be pivotable and/or rotatable. In an embodiment, a lower end of the second support **3300c, 3400c, 4200c** may be rotatable.

In an embodiment, the second support **3300c, 3400c, 4200c** may be raisable and/or lowerable. In an embodiment, an upper end of the second support **3300c, 3400c, 4200c** may be raisable and/or lowerable. In an embodiment, a lower end of the second support **3300c, 3400c, 4200c** may be raisable and/or lowerable.

Any suitable connection may be used for the second support **3300c, 3400c, 4200c**. For example, suitable connections include, but are not limited to, fittings and welds. Connections are well known in the art.

In an embodiment, an upper end of the second support **3300c, 3400c, 4200c** may be attached to an outer surface of

the second subassembly **33000b**, **34000b**, **42000b** by a connection. For example, suitable connections include, but are not limited to, bands, clamps, fittings, saddles and welds. In an embodiment, an upper end of the second support **3300c**, **3400c**, **4200c** may be attached to an outer surface of the second subassembly **33000b**, **34000b**, **42000b** by a band, a clamp and/or a saddle.

In an embodiment, the lower end of the second support **3300c**, **3400c**, **4200c** may be attached to the upper surface of the skid **3300a**, **3400a**, **4200a** (base or frame **3300e**, **3400e**, **4200e**) by a connection. For example, suitable connections include, but are not limited to, bands, clamps, fittings and welds. In an embodiment, the lower end of the second support **3300c**, **3400c**, **4200c** may be attached to the upper surface of the skid **3300a**, **3400a**, **4200a** (base or frame **3300e**, **3400e**, **4200e**) by a connection. In an embodiment, the lower end of the second support **3300c**, **3400c**, **4200c** may be attached to the upper surface of the skid **3300a**, **3400a**, **4200a** (base or frame **3300e**, **3400e**, **4200e**) by a connection. For example, suitable connections include, but are not limited to, bands, clamps, fittings and welds. In an embodiment, the lower end of the second support **3300c**, **3400c**, **4200c** may be attached to the upper surface of the skid **3300a**, **3400a**, **4200a** (base or frame **3300e**, **3400e**, **4200e**) by a connection. In an embodiment, the lower end of the second support **3300c**, **3400c**, **4200c** may be attached to the upper surface of the skid **3300a**, **3400a**, **4200a** (base or frame **3300e**, **3400e**, **4200e**) by a connection. For example, suitable connections include, but are not limited to, bands, clamps, fittings and welds.

Any suitable coupling may be used for the second support **3300c**, **3400c**, **4200c**. For example, suitable couplings include, but are not limited to bearings, hinges, pivots, sockets, and combinations thereof. In an embodiment, the coupling for the second support **3300c**, **3400c**, **4200c** may be a bearing. In an embodiment, the coupling for the second support **3300c**, **3400c**, **4200c** may be a box channel with a pivot pin.

In an embodiment, the second support **3300c**, **3400c**, **4200c** may have a coupling at or near an upper end. For example, suitable couplings include, but are not limited to bearings, hinges, pivots, sockets, and combinations thereof. In an embodiment, the second support **3300c**, **3400c**, **4200c** may have a bearing or a socket at or near an upper end. In an embodiment, the second support **3300c**, **3400c**, **4200c** may have a hinge or a pivot at or near an upper end.

In an embodiment, the second support **3300c**, **3400c**, **4200c** may have a coupling at or near a lower end. For example, suitable couplings include, but are not limited to bearings, hinges, pivots, sockets, and combinations thereof. In an embodiment, the second support **3300c**, **3400c**, **4200c** may have a bearing or a socket at or near a lower end. In an embodiment, the second support **3300c**, **3400c**, **4200c** may have a hinge or a pivot at or near a lower end.

In an embodiment, the second support **3300c**, **3400c**, **4200c** may pivot and/or rotate automatically and/or manually. In an embodiment, the second support **3300c**, **3400c**, **4200c** may pivot and/or rotate electro-mechanically, hydraulically, mechanically (e.g., geared) or pneumatically. In an embodiment, the second support **3300c**, **3400c**, **4200c** may pivot and/or rotate manually.

Any suitable extension may be used for the second support **3300c**, **3400c**, **4200c**. For example, suitable extensions include, but are not limited to articulated arms, extendable pistons, telescoping pipes, and combinations thereof. In an embodiment, the extension for the second support **3300c**, **3400c**, **4200c** may be an extendable piston. In an embodiment, the coupling for the second support **3300c**, **3400c**, **4200c** may be a telescoping pipe with a clevis pin.

In an embodiment, the second support **3300c**, **3400c**, **4200c** may have an extension at or near an upper end. For example, suitable extensions include, but are not limited to articulated arms, extendable pistons, telescoping pipes, and combinations thereof. In an embodiment, the second support **3300c**, **3400c**, **4200c** may have an extendable arm at or near

an upper end. In an embodiment, the second support **3300c**, **3400c**, **4200c** may have a telescoping pipe with a clevis pin at or near an upper end.

In an embodiment, the second support **3300c**, **3400c**, **4200c** may have an extension at or near a lower end. For example, suitable extensions include, but are not limited to articulated arms, extendable pistons, telescoping pipes, and combinations thereof. In an embodiment, the second support **3300c**, **3400c**, **4200c** may have an extendable piston at or near a lower end. In an embodiment, the second support **3300c**, **3400c**, **4200c** may have a telescoping pipe with a clevis pin at or near a lower end.

In an embodiment, the second support **3300c**, **3400c**, **4200c** may raise and/or lower automatically and/or manually. In an embodiment, the second support **3300c**, **3400c**, **4200c** may raise and/or lower electro-mechanically, hydraulically, mechanically (e.g., geared) or pneumatically. In an embodiment, the second support **3300c**, **3400c**, **4200c** may raise and/or lower manually.

In an embodiment, an upper end of the third support **3300d**, **3400d**, **4200d** may be mechanically coupled to a lower surface of the union system **33102**, **34102**, **42102** (e.g., a third body **33108c**, **34108c**, **42108c** of the union system **33102**, **34102**, **42102**); and the lower end of the third support **3300d**, **3400d**, **4200d** may be mechanically coupled to an upper surface of the base or frame **3300e**, **3400e**, **4200e**.

In an embodiment, the third support **3300d**, **3400d**, **4200d** may be stationary when the first support **3300b**, **3400b**, **4200b** and/or the second support **3300c**, **3400c**, **4200c** are pivotable and/or rotatable, raisable and/or lowerable, and any combination thereof.

In an embodiment, the third support **3300d**, **3400d**, **4200d** may be pivotable and/or rotatable. In an embodiment, an upper end of the third support **3300d**, **3400d**, **4200d** may be pivotable and/or rotatable. In an embodiment, the lower end of the third support **3300d**, **3400d**, **4200d** may be rotatable or stationary.

In an embodiment, the third support **3300d**, **3400d**, **4200d** may be raisable and/or lowerable. In an embodiment, an upper end of the third support **3300d**, **3400d**, **4200d** may be raisable and/or lowerable. In an embodiment, a lower end of the third support **3300d**, **3400d**, **4200d** may be raisable and/or lowerable.

Any suitable connection may be used for the third support **3300d**, **3400d**, **4200d**. For example, suitable connections include, but are not limited to, fittings and welds. Connections are well known in the art.

In an embodiment, an upper end of the third support **3300d**, **3400d**, **4200d** may be attached to an outer surface of the union system **33102**, **34102**, **42102** by a connection. For example, suitable connections include, but are not limited to, bands, clamps, fittings, saddles and welds. In an embodiment, an upper end of the third support **3300d**, **3400d**, **4200d** may be attached to an outer surface of the union system **33102**, **34102**, **42102** by a band or a clamp or a saddle.

In an embodiment, the lower end of the third support **3300d**, **3400d**, **4200d** may be attached to the upper surface of the skid **3300a**, **3400a**, **4200a** (base or frame **3300e**, **3400e**, **4200e**) by a connection. For example, suitable connections include, but are not limited to, bands, clamps, fittings and welds. In an embodiment, the lower end of the third support **3300d**, **3400d**, **4200d** may be attached to the upper surface of the skid **3300a**, **3400a**, **4200a** (base or frame **3300e**, **3400e**, **4200e**) by a connection. In an embodiment, the lower end of the third support **3300d**, **3400d**,

4200d may be attached to the upper surface of the skid 3300a, 3400a, 4200a (base or frame 3300e, 3400e, 4200e) by fittings or welds.

Any suitable coupling may be used for the third support 3300d, 3400d, 4200d. For example, suitable couplings include, but are not limited to bearings, hinges, pivots, sockets, and combinations thereof. In an embodiment, the coupling for the third support 3300d, 3400d, 4200d may be a bearing. In an embodiment, the coupling for the third support 3300d, 3400d, 4200d may be a box channel with a pivot pin.

In an embodiment, the third support 3300d, 3400d, 4200d may have a coupling at or near an upper end. For example, suitable couplings include, but are not limited to bearings, hinges, pivots, sockets, and combinations thereof. In an embodiment, the third support 3300d, 3400d, 4200d may have a bearing or a socket at or near an upper end. In an embodiment, the third support 3300d, 3400d, 4200d may have a hinge or a pivot at or near an upper end.

In an embodiment, the third support 3300d, 3400d, 4200d may have a coupling at or near a lower end. For example, suitable couplings include, but are not limited to bearings, hinges, pivots, sockets, and combinations thereof. In an embodiment, the third support 3300d, 3400d, 4200d may have a bearing or a socket at or near a lower end. In an embodiment, the third support 3300d, 3400d, 4200d may have a hinge or a pivot at or near a lower end.

In an embodiment, the third support 3300d, 3400d, 4200d may pivot and/or rotate automatically and/or manually. In an embodiment, the third support 3300d, 3400d, 4200d may pivot and/or rotate electro-mechanically, hydraulically, mechanically (e.g., geared) or pneumatically. In an embodiment, the third support 3300d, 3400d, 4200d may pivot and/or rotate manually.

Any suitable extension may be used for the third support 3300d, 3400d, 4200d. For example, suitable extensions include, but are not limited to articulated arms, extendable pistons, telescoping pipes, and combinations thereof. In an embodiment, the extension for the third support 3300d, 3400d, 4200d may be an extendable piston. In an embodiment, the extension for the third support 3300d, 3400d, 4200d may be a telescoping pipe with a clevis pin.

In an embodiment, the third support 3300d, 3400d, 4200d may have an extension at or near an upper end. For example, suitable extensions include, but are not limited to articulated arms, extendable pistons, telescoping pipes, and combinations thereof. In an embodiment, the third support 3300d, 3400d, 4200d may have an extendable arm at or near an upper end. In an embodiment, the third support 3300d, 3400d, 4200d may have a telescoping pipe with a clevis pin at or near an upper end.

In an embodiment, the third support 3300d, 3400d, 4200d may have an extension at or near a lower end. For example, suitable extensions include, but are not limited to articulated arms, extendable pistons, telescoping pipes, and combinations thereof. In an embodiment, the third support 3300d, 3400d, 4200d may have an extendable piston at or near a lower end. In an embodiment, the third support 3300d, 3400d, 4200d may have a telescoping pipe with a clevis pin at or near a lower end.

In an embodiment, the third support 3300d, 3400d, 4200d may raise and/or lower automatically and/or manually. In an embodiment, the third support 3300d, 3400d, 4200d may raise and/or lower electro-mechanically, hydraulically, mechanically (e.g., geared) or pneumatically. In an embodiment, the third support 3300d, 3400d, 4200d may raise and/or lower manually.

In an embodiment, the first support 3300b, 3400b, 4200b, the second support 3300c, 3400c, 4200c and/or the third support 3300d, 3400d, 4200d of the skid 3300a, 3400a, 4200a of the drilling mud screen system 3300, 3400, 4200 may be constructed of any suitable material. For example, suitable materials include, but are not limited to, any alloy steel suitable for a drilling mud application. In an embodiment, the first support 3300b, 3400b, 4200b, the second support 3300c, 3400c, 4200c, and/or the third support 3300d, 3400d, 4200d of the skid 3300a, 3400a, 4200a may be constructed of an alloy steel or equivalent material. See e.g., FIGS. 33A-33C, 34A-34B & 42A-42B. In an embodiment, the first support 3300b, 3400b, 4200b, the second support 3300c, 3400c, 4200c, and/or the third support 3300d, 3400d, 4200d of the skid 3300a, 3400a, 4200a may be constructed of a 304 stainless steel material. In an embodiment, the first support 3300b, 3400b, 4200b, the second support 3300c, 3400c, 4200c, and/or the third support 3300d, 3400d, 4200d of the skid 3300a, 3400a, 4200a may be unpainted. In an embodiment, the first support 3300b, 3400b, 4200b, the second support 3300c, 3400c, 4200c, and/or the third support 3300d, 3400d, 4200d of the skid 3300a, 3400a, 4200a may be painted.

In an embodiment, the base or frame 3300e, 3400e, 4200e of the skid 3300a, 3400a, 4200a of the drilling mud screen system 3300, 3400, 4200 may be constructed of any suitable material. For example, suitable materials include, but are not limited to, a concrete, a polymer, and any alloy steel suitable for a drilling mud application. In an embodiment, the base or frame 3300e, 3400e, 4200e may be constructed of a concrete. In an embodiment, the base or frame 3300e, 3400e, 4200e may be constructed of a polymer. In an embodiment, the base or frame 3300e, 3400e, 4200e of the skid 3300a, 3400a, 4200a may be constructed of an alloy steel or equivalent material. See e.g., FIGS. 33A-33C, 34A-34B & 42A-42B. In an embodiment, the base or frame 3300e, 3400e, 4200e of the skid 3300a, 3400a, 4200a may be constructed of a 304 stainless steel material. In an embodiment, the base or frame 3300e, 3400e, 4200e of the skid 3300a, 3400a, 4200a may be unpainted. In an embodiment, the base or frame 3300e, 3400e, 4200e of the skid 3300a, 3400a, 4200a may be painted.

Optional End Subassembly

FIG. 31 illustrates a detailed view of an optional end subassembly for a piston-style drilling mud screen system 3000, 3300, 3400 according to an embodiment of the present invention, providing a cross-over connection 3105 from a first subassembly 30000a, 33000a, 34000a and/or a second subassembly 30000b, 33000b, 34000b to an optional transducer subassembly 19100 (discussed below). As shown in FIG. 31, the optional end subassembly 3100 comprises a cross-over connection 3105 from a first subassembly 30000a, 33000a, 34000a and/or a second subassembly 30000b, 33000b, 34000b to an optional transducer subassembly 19100.

Optional Transducer Subassembly for Two-Piece Body and Piston Body

FIG. 19 illustrates a cross-sectional view of the drilling mud screen system in a monitoring configuration 1900 according to an embodiment of the present invention, showing an optional transducer subassembly 19100. As shown in FIG. 19, the drilling mud screen system 19200 has a first body 1905a having a first end 1910a and a second end 1915a, a first drilling mud inlet 1920a and a first drilling mud outlet 1925a, an end cap 1935, a first drilling mud screen access port 1930a, and an optional transducer subassembly 19100.

As shown in FIGS. 19 and 28, the drilling mud inlet 1920 of the drilling mud screen system 19200, 28200 may be fluidly connected to a drilling mud outlet 28125 of the transducer subassembly 19110, 28100 via a connection. Any suitable connection may be used for the drilling mud inlet 1920 and the drilling mud outlet 28125. For example, suitable connections include, but are not limited to, pipe fittings and welds. Connections are well known in the art. In an embodiment, the drilling mud inlet 1920 of the drilling mud screen system 19200, 28200 may be fluidly connected to a drilling mud outlet 28125 of a transducer subassembly 19100 via a weld.

FIG. 20A illustrates an upper, right side perspective view of an optional transducer subassembly 2000 according to an embodiment of the present invention; and FIG. 20B illustrates a side perspective view of the optional transducer subassembly of FIG. 20A. As shown in FIGS. 20A and 20B, the optional transducer subassembly 2000 has a body 2005 having a first end 2010 and a second end 2015, an inlet 2020 and an outlet 2025, a transducer port 2030, and a transducer 28105. See e.g., FIG. 28.

In an embodiment, the drilling mud inlet 2020 of the optional transducer subassembly 2000 may be fluidly connected to, for example, an outlet of a drilling mud pump via a connection; and the drilling mud outlet 2025 may be fluidly connected to, for example, an inlet of a drilling mud screen system via a connection. Any suitable connection may be used for the drilling mud inlet 2020 and the drilling mud outlet 2025. For example, suitable connections include, but are not limited to, pipe fittings and welds. Connections are well known in the art. In an embodiment, the drilling mud inlet 2020 of the optional transducer subassembly 2000 may be fluidly connected to, for example, an outlet of a drilling mud pump via a weld; and the drilling mud outlet 2025 of the optional transducer assembly 2000 may be fluidly connected to, for example, an inlet of a drilling mud screen system via a weld.

In an embodiment, the transducer access port 2030 of the optional transducer subassembly 2000 may be closed with a transducer via a fitting. Any suitable type of transducer may be used. For example, suitable types of transducers include, but are not limited to, displacement transducers, flow rate transducers, pressure transducers, temperature transducers and any combination thereof. Any suitable fitting may be used. For example, suitable fittings include, but are not limited to, pipe fittings. Fittings are well known in the art. In an embodiment, the transducer access port 2030 of the optional transducer subassembly 2000 may be closed with a pressure transducer via a 2-inch 1502 WECO union.

In an embodiment, a computing device (such as a rig computer) may include a bus that directly or indirectly couples the following devices: memory, one or more processors, one or more presentation components, one or more input/output (I/O) ports, I/O components, a user interface and a power supply. The computing device may include a variety of computer-readable media. The memory may include computer-storage media in the form of volatile and/or nonvolatile memory. The presentation component(s) present data indications to a user or other device. The user interface allows the user to input/output information to/from the computing device. The one or more I/O ports may allow the computing device to be logically coupled to other devices including a transducer 28105, and other I/O components, some of which may be built in. See e.g., FIG. 28. Examples of other I/O components include a printer, scanner, wireless device, and the like.

In an embodiment, the transducer access port 2030 of the optional transducer subassembly 2000 may be sealed with an end cap via an O-ring. Any suitable O-ring may be used. For example, suitable O-rings include, but are not limited to, 5 300 Series O-rings. O-rings are well known in the art.

In an embodiment, the body 2005 of the optional transducer subassembly 2000 may be constructed of any suitable material. For example, suitable materials include, but are not limited to, any alloy steel suitable for a drilling mud application. In an embodiment, the body 2005 may be constructed of an American Iron and Steel Industry (AISI) 4130/75k yield or equivalent material. See e.g., FIG. 2. In an embodiment, the inner surface of the body 2005 may be unpainted. In an embodiment, the outer surface of the body 2005 may be painted.

In an embodiment, the body 2005 has a first centerline 2045 and a length 2050. In an embodiment, the first centerline 2045 extends through the center of the drilling mud inlet 2020 to the drilling mud outlet 2025. The length 2050 of the body 2005 may be any suitable length. In an embodiment, the length 2050 of the body 2005 may be from about 10-inches to about 30-inches, and any range or value there between. In an embodiment, the length 2050 may be about 12-inches.

In an embodiment, the body 2005 has a second centerline 2055. In an embodiment, the second centerline 2055 extends through the center of the transducer access port 2030 to the first centerline 2045.

In an embodiment, the first centerline 2045 and the second centerline 2055 form a first angle 2060. In an embodiment, the first angle 2060 may be from about 20-degrees to about 120-degrees, and any range or value there between. In an embodiment, the first angle 2060 may be about 45-degrees. In an embodiment, the first angle 2060 may be about 90-degrees.

In an embodiment, the transducer access port 2030 may be offset from a first end 2010 of the body 2005. The transducer access port 2030 may be offset from a first end 40 2010 of the body 2005 at any suitable distance. In an embodiment, the second centerline 2055 may be offset from the first end 2010 of the body 2005 from about 6-inches to about 15-inches, and any range or value there between. In an embodiment, the second centerline 2055 may be offset from the first end 2010 of the body 2005 about 7-inches.

In an embodiment, the transducer access port 2030 may have any suitable inner diameter. In an embodiment, the inner diameter of the transducer access port 2030 may be from about 1-inches to about 3-inches, and any range or value there between. In an embodiment, the inner diameter of the transducer access port 2030 may be about 2-inches.

In an embodiment, the outer diameter of the transducer access port 2030 may be from about 1.5-inches to about 3.5-inches, and any range or value there between. In an embodiment, the outer diameter of the transducer access port 2030 may be about 2.5-inches.

In an embodiment, the drilling mud inlet 2020 may have any suitable inner diameter 2065; and the drilling mud inlet 2020 may have any suitable outer diameter 2070. In an embodiment, the inner diameter 2065 of the drilling mud inlet 2020 may be from about 3-inches to about 5-inches, and any range or value there between. In an embodiment, the inner diameter 2065 of the drilling mud inlet 2020 may be about 4-inches.

In an embodiment, the outer diameter 2070 of the drilling mud inlet 2020 may be from about 4.5-inches to about 6.5-inches, and any range or value there between. In an

embodiment, the outer diameter 2070 of the drilling mud inlet 2020 may be about 5.5-inches.

In an embodiment, the drilling mud outlet 2025 may have any suitable inner diameter 2065; and the drilling mud outlet 2025 may have any suitable outer diameter 2070. In an embodiment, the inner diameter 2065 of the drilling mud outlet 2025 may be from about 3-inches to about 5-inches, and any range or value there between. In an embodiment, the inner diameter 2065 of the drilling mud outlet 2025 may be about 4-inches.

In an embodiment, the outer diameter 2070 of the drilling mud outlet 2025 may be from about 4.5-inches to about 6.5-inches, and any range or value there between. In an embodiment, the outer diameter 2070 of the drilling mud outlet 2025 may be about 5.5-inches.

Drilling Mud Screen

The drilling mud screen 500 may be any suitable filter or screen capable of filtering or screening debris from drilling muds and completion fluids. For example, suitable drilling mud screens include, but are not limited to, drill screens and rod screens.

FIG. 5A illustrates an upper, cross-sectional view of a drilling mud screen according to an embodiment of the present invention, as discussed above. FIG. 5B illustrates a detailed view of A-A of FIG. 5A; FIG. 5C illustrates a detailed view of B of FIG. 5A; and FIG. 5D illustrates a detailed view of C of FIG. 5A. FIG. 5E illustrates an upper, right side perspective view of the drilling mud screen of FIG. 5A.

Optional Drilling Mud Screen

The drilling mud screen 2200 may be any suitable filter or screen capable of filtering or screening debris from drilling muds and completion fluids. For example, suitable drilling mud screens include, but are not limited to, drill screens and rod screens.

FIG. 22A illustrates an end view of an optional drilling mud screen 2200 according to an embodiment of the present invention; FIG. 22B illustrates a detailed, cross-sectional view of A-A of FIG. 22A, showing an optional drilling mud screen insert 22105, and optional first end retaining ring 22110, an optional filter length 22115, and an optional retaining ring 22120; FIG. 22C illustrates a detailed view of B of FIG. 22B; FIG. 22D illustrates a detailed, cross-sectional view of C-C of FIG. 22C; and FIG. 22E illustrates an upper, right perspective view of the drilling mud screen of FIGS. 22A-22B.

As shown in FIG. 22B, the drilling mud screen 2200 has a body 2205 having a first end 2210 and a second end 2215, a drilling mud inlet 2220, a drilling mud outlet 2225, a filter 2230 and an end cap 2235.

In an embodiment, the drilling mud inlet 2220 may be fluidly connected to, for example, an outlet of a drilling mud pump via a connection; and the drilling mud outlet 2225 may be fluidly connected to an inlet of a vibrator hose via a connection. Any suitable connection may be used for the drilling mud inlet 2220 and the drilling mud outlet 2225. For example, suitable connections include, but are not limited to, pipe fittings and welds. Connections are well known in the art. In an embodiment, the drilling mud inlet 2220 may be fluidly connected to, for example, an outlet of a drilling mud pump via a weld; and the drilling mud outlet 2225 may be fluidly connected to an inlet of a vibrator hose via a weld.

In an embodiment, the body 2205 of the drilling mud screen 2200 may be constructed of any suitable material. For example, suitable materials include, but are not limited to, any alloy steel or tool steel. In an embodiment, the body 2205 may be constructed of an AISI 4145 or equivalent

material. See e.g., FIGS. 5A-5E. In an embodiment, the body 2205 may be constructed of tool steel or equivalent material.

In an embodiment, the body 2205 of the drilling mud screen 2200 may have a hardened coating to reduce washing (i.e., erosion) of the screen 2200. For example, suitable hardened coatings include, but are not limited to, any Carbide coating or equivalent. In an embodiment, the body 2205 may have a Carbide coating with about 6% Cobalt binder or equivalent material.

In an embodiment, the body 2205 of the drilling mud screen 2200 has a centerline 2245 and a length 2250. In an embodiment, the centerline 2245 extends through the center of the drilling mud screen inlet 2220 to the end cap 2235. The length 2250 of the body 2205 may be any suitable length. In an embodiment, the length 2250 of the body 2205 may be from about 20-inches to about 30-inches, and any range or value there between. In an embodiment, the length 2250 may be about 25-inches.

In an embodiment, the drilling mud inlet 2220 of the drilling mud screen 2200 may have any suitable inner diameter 2265; and the drilling mud inlet 2220 may have any suitable outer diameter 2270. In an embodiment, the inner diameter 2265 of the drilling mud inlet 2220 may be from about 3-inches to about 5-inches, and any range or value there between. In an embodiment, the inner diameter 2265 of the drilling mud inlet 2220 may be about 3.9-inches.

In an embodiment, the outer diameter 2270 of the drilling mud inlet 2220 may be from about 4-inches to about 6-inches, and any range or value there between. In an embodiment, the outer diameter 2270 of the drilling mud inlet 2220 may be about 4-inches.

In an embodiment, the body 2205 of the drilling mud screen 2200 has a first portion 2275 and a second portion 2280. In an embodiment, the first portion 2275 of the body 2205 has a first length 22125; and the second portion 2280 of the body 2205 has a second length 22130. The first portion 2275 and the second portion 2280 may be any suitable length. In an embodiment, the first portion 2275 may have a first length 22125 from about 6-inches to about 10-inches, and any range or value there between; and the second portion 2280 may have a second length 22130 from about 14-inches to about 20-inches, and any range or value there between. In an embodiment, the first portion 2275 may have a first length 22125 of about 7.5-inches; and the second portion 2280 may have a second length 22130 of about 17.5-inches.

In an embodiment, the second portion 2280 of the body 2205 has a first section 22135, a second section 22145 and a third section 22155. In an embodiment, the first section 22135 has a third length 22140, the second section 22145 has a fourth length 22150 and the third section 22155 has a fifth length 22160. The first section 22135, the second section 22145 and the third section 22155 may be any suitable length. In an embodiment, the first section 22135 maybe up to about 20-25% longer than the second section 22145 and/or the third section 22155, resulting in increased flow efficiency and decreased erosion.

In an embodiment, the first section 22135 may have a third length 22140 from about 4-inches to about 8-inches, and any range or value there between. In an embodiment, the first section 22135 may have a third length 22140 of about 6-inches.

In an embodiment, the second section 22145 may have a fourth length 22150 from about 4-inches to about 8-inches,

and any range or value there between. In an embodiment, the second section 22145 may have a fourth length 22150 of about 5-inches.

In an embodiment, the third section 22155 may have a fifth length 22160 from about 4-inches to about 8-inches, and any range or value there between. In an embodiment, the third section 22155 may have a fifth length 22160 of about 5-inches.

In an embodiment, a second portion 2280 of the body 2205 of the drilling mud screen 2200 may have a filter 2230. In an embodiment, the filter 2230 may comprise a plurality of rods spaced a distance apart to form a filter. In an embodiment, the distance may be less than a particle size (e.g., diameter) desired to be filtered from the drilling mud. Particle filtration is well known in the art.

In an embodiment, the filter 2230 may comprise a formed sheet having drilled holes spaced a distance apart to form a filter. In an embodiment, the size of the holes (e.g., diameter) may be less than a particle size (e.g., diameter) desired to be filtered. Particle filtration is well known in the art.

In an embodiment, a second portion 2280 of the body 2205 of the drilling mud screen 2200 may have a drilling mud outlet 2225. In an embodiment, the drilling mud outlet 2225 may comprise a plurality of spaces (i.e., flow passages) between a plurality of rods. In an embodiment, the drilling mud outlet 2225 may comprise a plurality of holes (i.e., flow passages) drilled in a formed sheet.

In an embodiment, a first end 2210 of a first portion 2275 of the body 2205 of the drilling mud screen 2200 may have a first inner diameter 2285; and a second end 2215 of a second portion 2280 of the body 2205 may have a second inner diameter 2290.

In an embodiment, the first end 2210 of the first portion 2275 may be shaped to accept a puller/installer plate 975 of a drilling mud screen puller/installer tool 800, 900, as discussed below. See e.g., FIGS. 5A, 8A & 9A.

In an embodiment, the body 2205 and/or a filter 2230 of the drilling mud screen 2200 may have a tapered drilling mud flow path from a larger inner diameter to a smaller inner diameter to reduce washing (i.e., erosion) of the screen 2200.

In an embodiment, the first inner diameter 2285 of the first end 2210 of the body 2205 of the drilling mud screen 2200 may be from about 3-inches to about 5-inches, and any range or value there between. In an embodiment, the first inner diameter 2285 of the first end 2210 of the body 2205 may be about 3.9-inches.

FIG. 22D illustrates a detailed view of C-C of FIG. 22C, showing an outlet of a first portion 2275 of the body 2205 and an inlet of the second portion 2280 of the body 2205. In an embodiment, an inner diameter of an outlet of the first portion 2275 and an inlet of the second portion 2280 of the body 2205 may be from about 2-inches to about 3-inches, and any range or value there between. In an embodiment, the inner diameter of the outlet of the first portion 2275 of the body 2205 and the inlet of the second portion 2280 of the body 2205 may be about 2.5-inches.

In an embodiment, the outlet of the first portion 2275 and/or the inlet of the second portion 2280 of the body 2205 may be shaped to accept a rounded end 875, 975 of a drilling mud screen puller/installer tool 800, 900. See e.g., FIGS. 5B, 8B & 9B. See also FIGS. 12B, 13B & 29. In an embodiment, the inlet of the second portion 2280 of the body 2205 may have an inner shoulder to provide a pushing surface for the rounded end 875, 975 of the drilling mud screen puller/installer tool 800, 900. Id.

In an embodiment, the outlet of the first portion 2275 and/or the inlet of the second portion 2280 of the body 2205 may have a means to engage 2240 a drilling mud screen puller/installer tool 800, 900, as discussed below. See e.g., FIGS. 5A, 8A & 9A. The means to engage 2240 may be any suitable means to accept, and provide a pulling surface for, the drilling mud screen puller/installer tool 800, 900. For example, a suitable means to engage 2240 includes, but is not limited to, a "key" opening to rotationally engage an inner shoulder. In an embodiment, the outlet of the first portion 2275 and/or the inlet of the second portion 2280 of the body 2205 may be shaped to accept a puller/installer plate 870, 970 of a drilling mud screen puller/installer tool 800, 900. See e.g., FIGS. 5B, 8B & 9B. See also FIGS. 12A, 13A & 29. In an embodiment, the inlet of the second portion 2280 of the body 2205 may have an inner shoulder to provide a pulling surface for the puller/installer plate 870, 970 of the drilling mud screen puller/installer tool 800, 900. Id.

In an embodiment, the second inner diameter 2290 of the second end 2215 of the body 2205 of the drilling mud screen 2200 may be from about 2-inches to about 3-inches, and any range or value there between. In an embodiment, the second inner diameter 2290 of the second end 2215 of the body 2205 may be about 2.5-inches.

In an embodiment, the outer surface 2295 of the first portion 2275 of the body 2205 of the drilling mud screen 2200 may be adapted to engage one or more shoulders in an inner surface of the body 2205. In an embodiment, a first shoulder and a second shoulder of the body 2205 may be offset from a first end 2210 of the body 2205. Cf. FIGS. 4A & 5A. The first and second shoulders may be offset from the first end 2210 of the body 2205 at any suitable distance. In an embodiment, the first shoulder may be offset from the first end 2210 of the body 2205 from about 4-inches to about 8-inches, and any range or value there between; and the second shoulder may be offset from the first end 2210 of the body 2205 from about 5-inches to about 9-inches, and any range or value there between. In an embodiment, the first shoulder may be offset from the first end 2210 of the body 2205 about 4.8-inches; and the second shoulder may be offset from the first end 2210 of the body 2205 about 6.8-inches.

In an embodiment, the outer surface 2295 of the body 2205 of the drilling mud screen 2200 may be sealed against an inner surface of the body 2205 via an O-ring. Cf. FIGS. 4A & 5A. Any suitable O-ring may be used. For example, suitable O-rings include, but are not limited to, 300 Series O-rings. O-rings are well known in the art.

FIG. 22C illustrates a detailed view of B of FIG. 22B, showing a detailed view of a groove for an O-ring. In an embodiment, a groove for an O-ring may be offset from a first end 2210 of the body 2205 of the drilling mud screen 2200. The groove for the O-ring may be offset from the first end 2210 of the body 2205 at any suitable distance. In an embodiment, the groove for the O-ring may be offset from the first end 2210 of the body 2205 from about 4-inches to about 8-inches, and any range or value there between. In an embodiment, the groove for the O-ring may be offset from the first end 2210 of the body 2205 about 5.7-inches.

In an embodiment, the filter 2230 may have a plurality of rods spaced a distance apart to form a filter, or, alternatively, a formed sheet having drilled holes spaced a distance apart to form a filter. In an embodiment, the plurality of rods may be tapered from a larger outer diameter to a smaller outer diameter to encourage drilling mud flow to exit in straight lines through the drilling mud outlet 2225 (i.e., through flow

passages between the plurality rods) to reduce washing (i.e., erosion) of the screen 2200. In an embodiment, the filter 2230 may have a plurality of straight rows of holes drilled in a formed sheet to encourage drilling mud flow to exit in straight rows of strings through the drilling mud outlet 2225 (i.e., through straight flow passages of the drilled holes) to reduce washing (i.e., erosion) of the screen 2200.

In an embodiment, a first end of a filter 2230 may be connected to a second end 2215 of the body 2205 via a connection; and a second end of a filter 2230 may be connected to a first end of the end cap 2235 via a connection. Any suitable connection may be used for the filter 2230 and body 2205. For example, suitable connections include, but are not limited to, welds. Connections are well known in the art. In an embodiment, the first end of the filter 2230 may be connected to the second end 2215 of the body 2205 via a weld; and the second end of the filter 2230 may be connected to the first end of the end cap 2235 via a weld.

In an embodiment, the first end of the filter 2230 may fit into a first recess in the second end 2215 of the body 2205; and the second end of the filter 2230 may fit into a second recess in the first end of the end cap 2235. In an embodiment, the first recess and the second recess may be a plurality of recessed holes or a recessed groove. In an embodiment, the first recess and the second recess may be a plurality of recessed holes.

In an embodiment, the filter 2230 may be held together with a retaining ring. In an embodiment, the retaining ring may have a plurality of holes to hold the plurality of rods to form the filter 2230. In an embodiment, the plurality of rods may be connected to the plurality of holes in the retainer ring via a connection. Any suitable connection may be used for the filter 2230 and retaining ring. For example, suitable connections include, but are not limited to, welds. Connections are well known in the art. In an embodiment, the plurality of rods may be connected to the plurality of holes in the retainer ring via a weld.

In an embodiment, the filter 2230, including any retaining rings, of the drilling mud screen 2200 may be constructed of any suitable material. For example, suitable materials include, but are not limited to, any alloy steel or tool steel. In an embodiment, the filter 2230 may be constructed of 304 stainless steel material. See e.g., FIGS. 5A & 5E. In an embodiment, the filter 2230 may be constructed of AISI 4145 or equivalent material. In an embodiment, the filter 2230 may be constructed of D2 tool steel or equivalent material.

In an embodiment, the filter 2230 may have a hardened coating to reduce washing (i.e., erosion) of the screen 2200. For example, suitable hardened coatings include, but are not limited to, any Carbide coating or equivalent. In an embodiment, the filter 2230 may have a Carbide coating with about 6% Cobalt binder or equivalent material.

In an embodiment, the end cap 2235 of the drilling mud screen 2200 has an inner surface 2255. In an embodiment, the inner surface 2255 of the end cap 2235 of the drilling mud screen 2200 may redirect the flow to reduce washing (i.e., erosion) of the screen 2200. In an embodiment, the inner surface 2255 of the end cap 2235 of the drilling mud screen 2200 forms an inverted cone relative to the second end 2215 of the body 2205 of the drilling mud screen 2200 (i.e., an upstream pointing cone) to redirect the flow. In an embodiment, the tip of the inverted cone may have a rounded or squared shape.

In an embodiment, the body 2205 of the drilling mud screen 2200 has a centerline 2245 and a length 2250. In an embodiment, the centerline 2245 extends through the center

of the drilling mud screen inlet 2220 to the end cap 2235. In an embodiment, the centerline 2245 of the body 2205 of the drilling mud screen 2200 and the inner surface 2255 of the end cap 2235 form an angle 2260. In an embodiment, the angle 2260 may be from about 30-degrees to about 60-degrees, and any range or value there between. In an embodiment, the angle 2260 may be from about 35-degrees to about 45-degrees.

In an embodiment, the end cap 2235 of the drilling mud screen 2200 may be constructed of any suitable material. For example, suitable materials include, but are not limited to, any alloy steel or tool steel. In an embodiment, the end cap 2235 may be constructed of 304 stainless steel material or equivalent material. See e.g., FIGS. 5A & 5E. In an embodiment, the end cap 2235 may be constructed of AISI 4155 or equivalent material. In an embodiment, the end cap 2235 may be constructed of tool steel or equivalent material.

In an embodiment, the end cap 2235 of the drilling mud screen 2200 may have a hardened coating to reduce washing (i.e., erosion) of the screen 2200. For example, suitable hardened coatings include, but are not limited to, any Carbide coating or equivalent. In an embodiment, the end cap 2235 may have a Carbide coating with about 6% Cobalt binder or equivalent material.

FIG. 22E illustrates an upper, right side perspective view of the drilling mud screen of FIGS. 22A-22B. As shown in FIG. 22E, the drilling mud screen 2200 has a body 2205 having a first end 2210 and a second end 2215, a drilling mud inlet 2220, a drilling mud outlet 2225, a filter 2230 and an end cap 2235. In an embodiment, the body 2205 of the drilling mud screen 2200 has a first portion 2275 and a second portion 2280.

Alternative Reversed Drilling Mud Screen

The drilling mud screen 4140, 4240 may be any suitable filter or screen capable of filtering or screening debris from drilling muds and completion fluids. For example, suitable drilling mud screens include, but are not limited to, drill screens and rod screens.

FIG. 41A illustrates a cross-sectional view of an exemplary drilling mud screen system 4100 according to an embodiment of the invention, showing a reversed drilling mud screen 4140; and FIG. 41B illustrates a detailed view of the reversed drilling mud screen 4140 of FIG. 41A.

FIGS. 42A-1 and 42A-2 illustrate a cross-sectional view of an exemplary piston-style drilling mud screen system 4200 according to an embodiment of the invention, showing a reversed drilling mud screen 4240; and FIG. 42B illustrates a detailed view of the reversed drilling mud screen 4240 of FIGS. 42A-1 and 42A-2.

As shown in FIGS. 41A-42B, the drilling mud screen 4140, 4240 has a body 41205, 42205 having a first end 41210, 42210 and a second end 41215, 42215, a drilling mud inlet 41220, 42220, a drilling mud outlet 41225, 42225, a filter 41230, 42230 and an end cap 41235, 42235.

In an embodiment, the drilling mud inlet 41220, 42220 may be fluidly connected to, for example, an outlet of a drilling mud pump via a connection; and the drilling mud outlet 41225, 42225 may be fluidly connected to an inlet of a vibrator hose via a connection. Any suitable connection may be used for the drilling mud inlet 41220, 42220 and the drilling mud outlet 41225, 42225. For example, suitable connections include, but are not limited to, pipe fittings and welds. Connections are well known in the art. In an embodiment, the drilling mud inlet 41220, 42220 may be fluidly connected to, for example, an outlet of a drilling mud pump via a weld; and the drilling mud outlet 41225, 42225 may be fluidly connected to an inlet of a vibrator hose via a weld.

In an embodiment, the body **41205, 42205** of the drilling mud screen **4140, 4240** may be constructed of any suitable material. For example, suitable materials include, but are not limited to, any alloy steel or tool steel. In an embodiment, the body **41205, 42205** may be constructed of an AISI 4145 or equivalent material. In an embodiment, the body **41205, 42205** may be constructed of tool steel or equivalent material.

In an embodiment, the body **41205, 42205** of the drilling mud screen **4140, 4240** may have a hardened coating to reduce washing (i.e., erosion) of the screen **4140, 4240**. For example, suitable hardened coatings include, but are not limited to, any Carbide coating or equivalent. In an embodiment, the body **41205, 42205** may have a Carbide coating with about 6% Cobalt binder or equivalent material.

In an embodiment, the body **41205, 42205** of the drilling mud screen **4140, 4240** has a centerline **41245, 42245** and a length **41250, 42250**. In an embodiment, the centerline **41245, 42245** extends through the center of the drilling mud screen outlet **41225, 42225** to the end cap **41235, 42235**. The length **41250, 42250** of the body **41205, 42205** may be any suitable length. In an embodiment, the length **41250, 42250** of the body **41205, 42205** may be from about 20-inches to about 30-inches, and any range or value there between. In an embodiment, the length **41250, 42250** may be about 25-inches.

In an embodiment, the drilling mud outlet **41225, 42225** of the drilling mud screen **4140, 4240** may have any suitable inner diameter **565**; and the drilling mud outlet **41225, 42225** may have any suitable outer diameter **570**. In an embodiment, the inner diameter **565** of the drilling mud outlet **41225, 42225** may be from about 3-inches to about 5-inches, and any range or value there between. In an embodiment, the inner diameter **565** of the drilling mud outlet **41225, 42225** may be about 3.9-inches. See e.g., FIGS. 5A-5E.

In an embodiment, the outer diameter **570** of the drilling mud outlet **41225, 42225** may be from about 4-inches to about 6-inches, and any range or value there between. In an embodiment, the outer diameter **570** of the drilling mud inlet **41225, 42225** may be about 4-inches. See e.g., FIGS. 5A-5E.

In an embodiment, the body **41205, 42205** of the drilling mud screen **4140, 4240** has a first portion **41280, 42280** and a second portion **41275, 42275**. In an embodiment, the first portion **41280, 42280** of the body **41205, 42205** has a first length; and the second portion **41275, 42275** of the body **41205, 42205** has a second length. The first portion **41280, 42280** and the second portion **41275, 42275** may be any suitable length. In an embodiment, the first portion **41280, 42280** may have a first length from about 6-inches to about 10-inches; and the second portion **41275, 42275** may have a second length from about 14-inches to about 20-inches, and any range or value there between. In an embodiment, the first portion **41280, 42280** may have a first length of about 7.5-inches; and the second portion **41275, 42275** may have a second length of about 17.5-inches.

In an embodiment, a first portion **42280, 42280** of the body **41205, 42205** of the drilling mud screen **4140, 4240** may have a filter **41230, 42230**. In an embodiment, the filter **41230, 42230** may comprise a plurality of rods spaced a distance apart to form a filter. In an embodiment, the distance may be less than a particle size (e.g., diameter) desired to be filtered from the drilling mud. For example, the particle size desired to be filtered from drilling mud may be from about $\frac{3}{16}$ -inches and larger. For example, the particle

size desired to be filtered from the completion fluids may be from about 200 microns to about 2500 microns.

In an embodiment, the filter **41230, 42230** may comprise a formed sheet having drilled holes spaced a distance apart to form a filter. In an embodiment, the size of the holes (e.g., diameter) may be less than a particle size (e.g., diameter) desired to be filtered. For example, the particle size desired to be filtered from drilling mud may be from about $\frac{3}{16}$ -inches and larger. For example, the particle size desired to be filtered from the completion fluids may be from about 200 microns to about 2500 microns.

In an embodiment, a first portion **41280, 42280** of the body **41205, 42205** of the drilling mud screen **4140, 4240** may have a drilling mud inlet **41220, 42220**. In an embodiment, the drilling mud inlet **41220, 42220** may comprise a plurality of spaces (i.e., flow passages) between a plurality of rods. In an embodiment, the drilling mud inlet **41220, 42220** may comprise a plurality of holes (i.e., flow passages) drilled in a formed sheet. For example, the particle size desired to be filtered from drilling mud may be from about $\frac{3}{16}$ -inches and larger. For example, the particle size desired to be filtered from the completion fluids may be from about 200 microns to about 2500 microns.

In an embodiment, a first end **41210, 42210** of a first portion **41280, 42280** of the body **41205, 42205** of the drilling mud screen **4140, 4240** may have a first inner diameter **590**; and a second end **41215, 42215** of a second portion **41275, 42275** of the body **41205, 42205** may have a second inner diameter **585**. See e.g., FIGS. 5A-5E.

In an embodiment, the body **41205, 42205** and/or a filter **41230, 42230** of the drilling mud screen **4140, 4240** may have a tapered drilling mud flow path from a larger inner diameter to a smaller inner diameter to reduce washing (i.e., erosion) of the screen **4140, 4240**.

In an embodiment, the first inner diameter **590** of the first end **41210, 42210** of the body **41205, 42205** of the drilling mud screen **4140, 4240** may be from about 2-inches to about 3-inches, and any range or value there between. In an embodiment, the first inner diameter **590** of the first end **41210, 42210** of the body **41205, 42205** may be about 2.3-inches.

In an embodiment, an inner diameter of an outlet of the first portion **41280, 42280** and an inlet of the second portion **41275, 42275** of the body **41205, 42205** may be from about 2-inches to about 3-inches, and any range or value there between. In an embodiment, the inner diameter of the outlet of the first portion **575** of the body **505** and the inlet of the second portion **590** of the body **505** may be about 2.5-inches.

In an embodiment, the second inner diameter **585** of the second end **41215, 42215** of the body **41205, 42205** of the drilling mud screen **4140, 4240** may be from about 2-inches to about 5-inches, and any range or value there between. In an embodiment, the second inner diameter **585** of the second end **41215, 42215** of the body **41205, 42205** may be about 3.9-inches.

In an embodiment, the outer surface **595** of the second portion **41275, 42275** of the body **41205, 42205** of the drilling mud screen **4140, 4240** may be adapted to engage one or more shoulders in an inner surface of the body **4240, 4240**. In an embodiment, a first shoulder and a second shoulder of the body **41205, 42205** may be offset from a second end **41215, 42215** of the body **41205, 42205**. Cf. FIGS. 4A & 5A. The first and second shoulders may be offset from the second end **41215, 42215** of the body **41205, 42205** at any suitable distance. In an embodiment, the first shoulder may be offset from the second end **41215, 42215** of the body **41205, 42205** from about 4-inches to about

8-inches; and the second shoulder may be offset from the second end **41215, 42215** of the body **41205, 42205** from about 5-inches to about 9-inches, and any range or value there between. In an embodiment, the first shoulder may be offset from the second end **41215, 42215** of the body **41205, 42205** about 4.8-inches; and the second shoulder may be offset from the second end **41215, 42215** of the body **41205, 42205** about 6.8-inches.

In an embodiment, the outer surface **595** of the body **41205, 42205** of the drilling mud screen **4140, 4240** may be sealed against an inner surface of the body **41205, 42205** via an O-ring. Cf. FIGS. **4A & 5A**. Any suitable O-ring may be used. For example, suitable O-rings include, but are not limited to, 300 Series O-rings. O-rings are well known in the art.

In an embodiment, a groove for an O-ring may be offset from a second end **41215, 42215** of the body **41205, 42205** of the drilling mud screen **4140, 4240**. The groove for the O-ring may be offset from the second end **41215, 42215** of the body **41205, 42205** at any suitable distance. In an embodiment, the groove for the O-ring may be offset from the second end **42215, 42215** of the body **41205, 42205** from about 4-inches to about 8-inches, and any range or value there between. In an embodiment, the groove for the O-ring may be offset from the second end **41215, 42215** of the body **41205, 42205** about 5.7-inches.

In an embodiment, the filter **41230, 42230** may have a plurality of rods spaced a distance apart to form a filter, or, alternatively, a formed sheet having drilled holes spaced a distance apart to form a filter. In an embodiment, the plurality of rods may be tapered from a larger outer diameter to a smaller outer diameter to encourage drilling mud flow to enter in straight lines through the drilling mud inlet **41225, 42225** (i.e., through flow passages between the plurality rods) to reduce washing (i.e., erosion) of the screen **4140, 4240**. In an embodiment, the filter **41230, 42230** may have a plurality of straight rows of holes drilled in a formed sheet to encourage drilling mud flow to enter in straight rows of strings through the drilling mud inlet **41226, 42225** (i.e., through straight flow passages of the drilled holes) to reduce washing (i.e., erosion) of the screen **4140, 4240**.

In an embodiment, a first end of a filter **41230, 42230** may be connected to a second end of the end cap **41235, 42235** via a connection; and a second end of a filter **41230, 42230** may be connected to a first end **41210, 42210** of the body **41205, 42205** via a connection. Any suitable connection may be used for the filter **41230, 42230** and end cap **41235, 42235**. For example, suitable connections include, but are not limited to, welds. Connections are well known in the art. In an embodiment, the first end of the filter **41230, 42230** may be connected to the second end of the end cap **41235, 42235** via a weld; and the second end of the filter **41230, 42230** may be connected to the first end **41215, 42215** of the body **41205, 42205** via a weld.

In an embodiment, the first end of the filter **41230, 42230** may fit into a first recess in the second end of the end cap **41235, 42235**; and the second end of the filter **41230, 42230** may fit into a second recess in the first end **41210, 42210** of the body **41205, 42205**. In an embodiment, the first recess and the second recess may be a plurality of recessed holes or a recessed groove. In an embodiment, the first recess and the second recess may be a plurality of recessed holes.

In an embodiment, the filter **41230, 42230** may be held together with a retaining ring. In an embodiment, the retaining ring may have a plurality of holes to hold the plurality of rods to form the filter **41230, 42230**. In an embodiment, the plurality of rods may be connected to the plurality of

holes in the retainer ring via a connection. Any suitable connection may be used for the filter **41230, 42230** and retaining ring. For example, suitable connections include, but are not limited to, welds. Connections are well known in the art. In an embodiment, the plurality of rods may be connected to the plurality of holes in the retainer ring via a weld.

In an embodiment, the filter **41230, 42230**, including any retaining rings, of the drilling mud screen **4140, 4240** may be constructed of any suitable material. For example, suitable materials include, but are not limited to, any alloy steel. In an embodiment, the filter **41230, 42230** may be constructed of 304 stainless steel material. In an embodiment, the filter **41230, 42230** may have a hardened coating to reduce washing (i.e., erosion) of the screen **4140, 4240**.

In an embodiment, the end cap **41235, 42235** of the drilling mud screen **4140, 4240** has an outer surface **41255, 42255**. In an embodiment, the outer surface **41255, 42255** of the end cap **41235, 42235** of the drilling mud screen **4140, 4240** may redirect the flow to reduce washing (i.e., erosion) of the screen **4140, 4240**. In an embodiment, the outer surface **41255, 42255** of the end cap **41235, 42235** of the drilling mud screen **4140, 4240** forms an inverted cone relative to the first end **41210, 42210** of the body **41205, 42205** of the drilling mud screen **4140, 4240** (i.e., an upstream pointing cone) to redirect the flow. In an embodiment, the tip of the inverted cone may have a rounded or squared shape. See e.g., FIGS. **5A-5E**.

In an embodiment, the body **41205, 42205** of the drilling mud screen **4140, 4240** has a centerline **41245, 42245** and a length **41250, 42250**. In an embodiment, the centerline **41245, 42245** extends through the center of the drilling mud screen outlet **41225, 42225** to the end cap **41235, 42235**. In an embodiment, the centerline **41245, 42245** of the body **41205, 42205** of the drilling mud screen **4140, 4240** and the outer surface **41255, 42255** of the end cap **41235, 42235** form an angle **41260, 42260**. In an embodiment, the angle **41260, 42260** may be from about 30-degrees to about 90-degrees, and any range or value there between. In an embodiment, the angle **41260, 42260** may be from about 35-degrees to about 45-degrees.

In an embodiment, the end cap **41235, 42235** of the drilling mud screen **4140, 4240** may be constructed of any suitable material. For example, suitable materials include, but are not limited to, any alloy steel. In an embodiment, the end cap **41235, 42235** may be constructed of 304 stainless steel material. In an embodiment, the end cap **41235, 42235** of the drilling mud screen **4140, 4240** may have a hardened coating to reduce washing (i.e., erosion) of the screen **4140, 4240**. For example, suitable hardened coatings include, but are not limited to, any Carbide coating or equivalent. In an embodiment, the end cap **41235, 42235** may have a Carbide coating with about 6% Cobalt binder or equivalent material.

Second Alternative Reversed Drilling Mud Screen

The drilling mud screen **4140, 4240** may be any suitable filter or screen capable of filtering or screening debris from drilling muds and completion fluids. For example, suitable drilling mud screens include, but are not limited to, drill screens and rod screens.

FIG. **41A** illustrates a cross-sectional view of an exemplary drilling mud screen system **4100** according to an embodiment of the invention, showing a reversed drilling mud screen **4140**; and FIG. **41B** illustrates a detailed view of the reversed drilling mud screen **4140** of FIG. **41A**.

FIG. **42A** illustrates a cross-sectional view of an exemplary piston-style drilling mud screen system **4200** according to an embodiment of the invention, showing a reversed

drilling mud screen 4240; and FIG. 42B illustrates a detailed view of the reversed drilling mud screen 4240 of FIG. 42A.

As shown in FIGS. 41A-42B, the drilling mud screen 4140, 4240 has a body 41205, 42205 having a first end 41210, 42210 and a second end 41215, 42215, a drilling mud inlet 41220, 42220, a drilling mud outlet 41225, 42225, a filter 41230, 42230 and an end cap 41235, 42235.

In an embodiment, the drilling mud inlet 41220, 42220 may be fluidly connected to, for example, an outlet of a drilling mud pump via a connection; and the drilling mud outlet 41225, 42225 may be fluidly connected to an inlet of a vibrator hose via a connection. Any suitable connection may be used for the drilling mud inlet 41220, 42220 and the drilling mud outlet 41225, 42225. For example, suitable connections include, but are not limited to, pipe fittings and welds. Connections are well known in the art. In an embodiment, the drilling mud inlet 41220, 42220 may be fluidly connected to, for example, an outlet of a drilling mud pump via a weld; and the drilling mud outlet 41225, 42225 may be fluidly connected to an inlet of a vibrator hose via a weld.

In an embodiment, the body 41205, 42205 of the drilling mud screen 4140, 4240 may be constructed of any suitable material. For example, suitable materials include, but are not limited to, any alloy steel or tool steel. In an embodiment, the body 41205, 42205 may be constructed of an AISI 4145 or equivalent material. In an embodiment, the body 41205, 42205 may be constructed of tool steel or equivalent material.

In an embodiment, the body 41205, 42205 of the drilling mud screen 4140, 4240 may have a hardened coating to reduce washing (i.e., erosion) of the screen 4140, 4240. For example, suitable hardened coatings include, but are not limited to, any Carbide coating or equivalent. In an embodiment, the body 41205, 42205 may have a Carbide coating with about 6% Cobalt binder or equivalent material.

In an embodiment, the body 41205, 42205 of the drilling mud screen 4140, 4240 has a centerline 41245, 42245 and a length 41250, 42250. In an embodiment, the centerline 41245, 42245 extends through the center of the drilling mud screen outlet 41225, 42225 of the body 41205, 42205 to the end cap 41235, 42235. The length 41250, 42250 of the body 41205, 42205 may be any suitable length. In an embodiment, the length 41250, 42250 of the body 41205, 42205 may be from about 20-inches to about 30-inches, and any range or value there between. In an embodiment, the length 41250, 42250 may be about 25-inches.

In an embodiment, the drilling mud outlet 41225, 42225 of the drilling mud screen 4140, 4240 may have any suitable inner diameter 2265; and the drilling mud outlet 41225, 42225 may have any suitable outer diameter 2270. In an embodiment, the inner diameter 2265 of the drilling mud outlet 41225, 42225 may be from about 3-inches to about 5-inches, and any range or value there between. In an embodiment, the inner diameter 2265 of the drilling mud outlet 41225, 42225 may be about 3.9-inches. See e.g., FIGS. 22A-22E.

In an embodiment, the outer diameter 2270 of the drilling mud outlet 41225, 42225 may be from about 4-inches to about 6-inches, and any range or value there between. In an embodiment, the outer diameter 2270 of the drilling mud outlet 41225, 42225 may be about 5-inches. See e.g., FIGS. 22A-22E.

In an embodiment, the body 41205, 42205 of the drilling mud screen 4140, 4240 has a first portion 41280, 42280 and a second portion 41275, 42275. In an embodiment, the first portion 41280, 42280 of the body 41205, 42205 has a first length 22130; and the second portion 41275, 42275 of the

body 41205, 42205 has a second length 22125. The first portion 41280, 42280 and the second portion 41275, 42275 may be any suitable length. In an embodiment, the first portion 41280, 42280 may have a first length 22130 from about 6-inches to about 10-inches, and any range or value there between; and the second portion 41275, 42275 may have a second length 22125 from about 14-inches to about 20-inches, and any range or value there between. In an embodiment, the first portion 41280, 42280 may have a first length 22130 of about 7.5-inches; and the second portion 41275, 42275 may have a second length 22125 of about 17.5-inches. See e.g., FIGS. 22A-22E.

In an embodiment, the first portion 41280, 42280 of the body 41205, 42205 has a first section 22155, a second section 22145 and a third section 22135. In an embodiment, the first section 22155 has a third length 22160, the second section 22145 has a fourth length 22150 and the third section 22135 has a fifth length 22140. The first section 22155, the second section 22145 and the third section 22135 may be any suitable length. In an embodiment, the first section 22155 maybe up to about 20-25% longer than the second section 22145 and/or the third section 22135, resulting in increased flow efficiency and decreased erosion. See e.g., FIGS. 22A-22E.

In an embodiment, the first section 22155 may have a third length 22160 from about 4-inches to about 8-inches, and any range or value there between. In an embodiment, the first section 22155 may have a third length 22160 of about 6-inches. See e.g., FIGS. 22A-22E.

In an embodiment, the second section 22145 may have a fourth length 22150 from about 4-inches to about 8-inches, and any range or value there between. In an embodiment, the second section 22145 may have a fourth length 22150 of about 5-inches. See e.g., FIGS. 22A-22E.

In an embodiment, the third section 22135 may have a fifth length 22140 from about 4-inches to about 8-inches, and any range or value there between. In an embodiment, the third section 22135 may have a fifth length 22140 of about 5-inches. See e.g., FIGS. 22A-22E.

In an embodiment, a first portion 41280, 42280 of the body 41205, 42205 of the drilling mud screen 4140, 4240 may have a filter 41230, 42230. In an embodiment, the filter 41230, 42230 may comprise a plurality of rods spaced a distance apart to form a filter. In an embodiment, the distance may be less than a particle size (e.g., diameter) desired to be filtered from the drilling mud. Particle filtration is well known in the art.

In an embodiment, the filter 41230, 42230 may comprise a formed sheet having drilled holes spaced a distance apart to form a filter. In an embodiment, the size of the holes (e.g., diameter) may be less than a particle size (e.g., diameter) desired to be filtered. Particle filtration is well known in the art.

In an embodiment, a first portion 41280, 42280 of the body 41205, 42205 of the drilling mud screen 4140, 4240 may have a drilling mud inlet 41220, 42220. In an embodiment, the drilling mud inlet 41220, 42220 may comprise a plurality of spaces (i.e., flow passages) between a plurality of rods. In an embodiment, the drilling mud inlet 41220, 42220 may comprise a plurality of holes (i.e., flow passages) drilled in a formed sheet. For example, the particle size desired to be filtered from drilling mud may be from about $\frac{3}{16}$ -inches and larger. For example, the particle size desired to be filtered from the completion fluids may be from about 200 microns to about 2500 microns.

In an embodiment, a first end 41210, 42210 of a first portion 41280, 42280 of the body 41205, 42205 of the

drilling mud screen 4140, 4240 may have a first inner diameter 2285; and a second end 41215, 42215 of a second portion 41275, 42275 of the body 41205, 42205 may have a second inner diameter 2290. See e.g., FIGS. 22A-22E.

In an embodiment, the body 41205, 42205 and/or a filter 41230, 42230 of the drilling mud screen 4140, 4240 may have a tapered drilling mud flow path from a larger inner diameter to a smaller inner diameter to reduce washing (i.e., erosion) of the screen 4140, 4240.

In an embodiment, the first inner diameter 2290 of the first end 41210, 42210 of the body 41205, 42205 of the drilling mud screen 4140, 4240 may be from about 2-inches to about 2-inches, and any range or value there between. In an embodiment, the first inner diameter 2290 of the first end 41210, 42210 of the body 41205, 42205 may be about 2.5-inches.

In an embodiment, the second inner diameter 2285 of the second end 41215, 42215 of the body 41205, 42205 of the drilling mud screen 4140, 4240 may be from about 3-inches to about 5-inches, and any range or value there between. In an embodiment, the second inner diameter 2285 of the second end 41215, 42215 of the body 41205, 42205 may be about 3.9-inches.

In an embodiment, the first inner diameter 2290 of the first end 41210, 42210 of the body 41205, 42205 of the drilling mud screen 4140, 4240 may be from about 2-inches to about 3-inches, and any range or value there between. In an embodiment, the first inner diameter 2290 of the first end 41210, 42210 of the body 41205, 42205 may be about 2.3-inches.

In an embodiment, an inner diameter of an outlet of the first portion 41280, 42280 and an inlet of the second portion 41275, 42275 of the body 41205, 42205 may be from about 2-inches to about 3-inches, and any range or value there between. In an embodiment, the inner diameter of the outlet of the first portion 41280, 42280 of the body 41205, 42205 and the inlet of the second portion 41275, 42275 of the body 41205, 42205 may be about 2.5-inches.

In an embodiment, the outer surface 2295 of the second portion 41275, 42275 of the body 41205, 42205 of the drilling mud screen 4140, 4240 may be adapted to engage one or more shoulders in an inner surface of the second body 4105b, 4205b. In an embodiment, a first shoulder and a second shoulder of the body 41205, 42205 may be offset from a second end 41215, 42215 of the body 41205, 42205. The first and second shoulders may be offset from the second end 41215, 42215 of the body 41205, 42205 at any suitable distance. In an embodiment, the first shoulder may be offset from the second end 41215, 42215 of the body 41205, 42205 from about 4-inches to about 8-inches, and any range or value there between; and the second shoulder may be offset from the second end 41215, 42215 of the body 41205, 42205 from about 5-inches to about 9-inches, and any range or value there between. In an embodiment, the first shoulder may be offset from the second end 41215, 42215 of the body 41205, 42205 about 4.8-inches; and the second shoulder may be offset from the second end 41215, 42215 of the body 41205, 42205 about 6.8-inches. See e.g., FIGS. 22A-22E.

In an embodiment, the outer surface 2295 of the body 41205, 42205 of the drilling mud screen 4140, 4240 may be sealed against an inner surface of the second body 4105b, 4205b via an O-ring. Any suitable O-ring may be used. For example, suitable O-rings include, but are not limited to, 300 Series O-rings. O-rings are well known in the art. See e.g., FIGS. 22A-22E.

In an embodiment, the filter 41230, 42230 may have a plurality of rods spaced a distance apart to form a filter, or,

alternatively, a formed sheet having drilled holes spaced a distance apart to form a filter. In an embodiment, the plurality of rods may be tapered from a larger outer diameter to a smaller outer diameter to encourage drilling mud flow to enter in straight lines through the drilling mud inlet 41220, 42220 (i.e., through flow passages between the plurality rods) to reduce washing (i.e., erosion) of the screen 4140, 4240. In an embodiment, the filter 41230, 42230 may have a plurality of straight rows of holes drilled in a formed sheet to encourage drilling mud flow to enter in straight rows of strings through the drilling mud inlet 41220, 42220 (i.e., through straight flow passages of the drilled holes) to reduce washing (i.e., erosion) of the screen 4140, 4240.

In an embodiment, a first end of a filter 41230, 42230 may be connected to a second end of the end cap 41235, 42235 via a connection; and a second end of a filter 41230, 42230 may be connected to a first end 41210, 42210 of the body 41205, 42205 via a connection. Any suitable connection may be used for the filter 41230, 42230 and end cap 41235, 42235. For example, suitable connections include, but are not limited to, welds. Connections are well known in the art. In an embodiment, and the first end of the filter 41230, 42230 may be connected to the second end of the end cap 41235, 42235 via a weld; and the second end of the filter 41230, 42230 may be connected to the first end 41210, 42210 of the body 41205, 42205 via a weld.

In an embodiment, the first end of the filter 41230, 42230 may fit into a first recess in the second end of the end cap 41235, 42235; and the second end of the filter 41230, 42230 may fit into a second recess in the first end 41210, 42210 of the body 41205, 42205. In an embodiment, the first recess and the second recess may be a plurality of recessed holes or a recessed groove. In an embodiment, the first recess and the second recess may be a plurality of recessed holes.

In an embodiment, the filter 41230, 42230 may be held together with a retaining ring. In an embodiment, the retaining ring may have a plurality of holes to hold the plurality of rods to form the filter 41230, 42230. In an embodiment, the plurality of rods may be connected to the plurality of holes in the retainer ring via a connection. Any suitable connection may be used for the filter 41230, 42230 and retaining ring. For example, suitable connections include, but are not limited to, welds. Connections are well known in the art. In an embodiment, the plurality of rods may be connected to the plurality of holes in the retainer ring via a weld.

In an embodiment, the filter 41230, 42230, including any retaining rings, of the drilling mud screen 4140, 4240 may be constructed of any suitable material. For example, suitable materials include, but are not limited to, any alloy steel or tool steel. In an embodiment, the filter 41230, 42230 may be constructed of 304 stainless steel material. In an embodiment, the filter 41230, 42230 may be constructed of AISI 4145 or equivalent material. In an embodiment, the filter 41230, 42230 may be constructed of D2 tool steel or equivalent material.

In an embodiment, the filter 41230, 42230 may have a hardened coating to reduce washing (i.e., erosion) of the screen 4140, 4240. For example, suitable hardened coatings include, but are not limited to, any Carbide coating or equivalent. In an embodiment, the filter 41230, 42230 may have a Carbide coating with about 6% Cobalt binder or equivalent material.

In an embodiment, the end cap 41235, 42235 of the drilling mud screen 4140, 4240 has an outer surface 41255, 42255. In an embodiment, the outer surface 41255, 42255 of the end cap 41235, 42235 of the drilling mud screen 4140,

4240 may redirect the flow to reduce washing (i.e., erosion) of the screen 4140, 4240. In an embodiment, the outer surface 41255, 42255 of the end cap 41235, 42235 of the drilling mud screen 4140, 4240 forms an inverted cone relative to the first end 41210, 42210 of the body 41205, 42205 of the drilling mud screen 4140, 4240 (i.e., an upstream pointing cone) to redirect the flow. In an embodiment, the tip of the inverted cone may have a rounded or squared shape.

In an embodiment, the body 41205, 42205 of the drilling mud screen 4140, 4240 has a centerline 41245, 42245 and a length 41250, 42250. In an embodiment, the centerline 41245, 42245 extends through the center of the drilling mud screen outlet 41225, 42225 to the end cap 41235, 42235. In an embodiment, the centerline 41245, 42245 of the body 41205, 42205 of the drilling mud screen 4140, 4240 and the outer surface 41255, 42255 of the end cap 41235, 42235 form an angle 41260, 42260. In an embodiment, the angle 41260, 42260 may be from about 30-degrees to about 90-degrees, and any range or value there between. In an embodiment, the angle 41260, 42260 may be from about 35-degrees to about 45-degrees.

In an embodiment, the end cap 41235, 42235 of the drilling mud screen 4140, 4240 may be constructed of any suitable material. For example, suitable materials include, but are not limited to, any alloy steel or tool steel. In an embodiment, the end cap 41235, 42235 may be constructed of 304 stainless steel material or equivalent material. In an embodiment, the end cap 41235, 42235 may be constructed of AISI 4155 or equivalent material. In an embodiment, the end cap 41235, 42235 may be constructed of tool steel or equivalent material.

In an embodiment, the end cap 41235, 42235 of the drilling mud screen 4140, 4240 may have a hardened coating to reduce washing (i.e., erosion) of the screen 4140, 4240. For example, suitable hardened coatings include, but are not limited to, any Carbide coating or equivalent. In an embodiment, the end cap 41235, 42235 may have a Carbide coating with about 6% Cobalt binder or equivalent material.

Optional Drilling Mud Screen Insert

FIG. 23 illustrates a cross-sectional view of a mud screen system according to an embodiment of the present invention, showing an optional drilling mud screen insert 23105 inserted into a drilling mud screen 2340. As shown in FIG. 23, the drilling mud screen system 700, 1900, 2100 has an optional drilling mud screen insert 23105 inserted into a drilling mud screen 2340 to reduce the washing (i.e., erosion) of the drilling mud screen 2340. In an embodiment, the optional drilling mud screen insert 23105 may be inserted into a first end 510, 2210 of the drilling mud screen 2340. See e.g., FIGS. 5 & 22. In an embodiment, the optional drilling mud screen insert 23105 may be brazed or welded to the drilling mud screen 2340.

FIG. 24A illustrates an end view of an optional drilling mud screen insert according to an embodiment of the present invention; FIG. 24B illustrates a detailed, cross-sectional view of A-A of FIG. 24A, showing an inlet of the drilling mud screen insert and an outlet of the drilling mud screen insert; and FIG. 24C illustrates an upper, right perspective view of the optional drilling mud screen insert of FIGS. 24A-24B. As shown in FIG. 24B, the optional drilling mud screen insert 2400 has a body 2405 having a first end 2410 and a second end 2415, a drilling mud inlet 2420 and a drilling mud outlet 2425.

In an embodiment, the body 2405 of the optional drilling mud screen insert 2400 may be constructed of any suitable material. For example, suitable materials include, but are not

limited to, any alloy steel or tool steel. In an embodiment, the body 2405 may be constructed of an AISI 4145 or equivalent material. See e.g., FIGS. 5A-5E. In an embodiment, the body 2405 may be constructed of tool steel or equivalent material.

In an embodiment, the body 2405 of the optional drilling mud screen insert 2400 may have a hardened coating to reduce washing (i.e., erosion) of the insert 2400. For example, suitable hardened coatings include, but are not limited to, any Carbide coating or equivalent. In an embodiment, the body 2405 may have a Carbide coating with about 6% Cobalt binder or equivalent material.

In an embodiment, the body 2405 of the optional drilling mud screen insert 2400 has a centerline 2445 and a length 2450. In an embodiment, the centerline 2445 extends through the center of the drilling mud inlet 2420 to the drilling mud outlet 2425. The length 2450 of the body 2405 may be any suitable length. In an embodiment, the length 2450 of the body 2405 may be from about 5-inches to about 10-inches, and any range or value there between. In an embodiment, the length 2450 may be about 6.9-inches.

In an embodiment, the drilling mud inlet 2420 of the optional drilling mud screen insert 2400 may have any suitable inner diameter 2465; and the drilling mud inlet 2420 may have any suitable outer diameter 2470. In an embodiment, the inner diameter 2465 of the drilling mud inlet 2450 may be from about 3-inches to about 5-inches, and any range or value there between. In an embodiment, the inner diameter 2465 of the drilling mud inlet 2420 may be about 3.9-inches.

In an embodiment, the outer diameter 2470 of the drilling mud inlet 2420 may be from about 4-inches to about 6-inches, and any range or value there between. In an embodiment, the outer diameter 2470 of the drilling mud inlet 2420 may be about 4-inches.

In an embodiment, the drilling mud outlet 2425 of the optional drilling mud screen insert 2400 may have any suitable inner diameter 2468; and the drilling mud outlet 2425 may have any suitable outer diameter 2472. In an embodiment, the inner diameter 2468 of the drilling mud outlet 2425 may be from about 2-inches to about 5-inches, and any range or value there between. In an embodiment, the inner diameter 2468 of the drilling mud outlet 2425 may be about 3-inches.

In an embodiment, the outer diameter 2472 of the drilling mud outlet 2425 may be from about 3.5-inches to about 6-inches, and any range or value there between. In an embodiment, the outer diameter 2472 of the drilling mud outlet 2425 may be about 3.5-inches.

In an embodiment, the body 2405 of the optional drilling mud screen insert 2400 has a first portion 2475 and a second portion 2480. In an embodiment, the first portion 2475 of the body 2405 has a first length 2478; and the second portion 2480 of the body 2405 has a second length 2482. The first portion 2475 and the second portion 2480 may be any suitable length. In an embodiment, the first portion 2475 may have a first length 2478 from about 1-inch to about 3-inches, and any range or value there between; and the second portion 2480 may have a second length 2482 from about 3-inches to about 7-inches, and any range or value there between. In an embodiment, the first portion 2475 may have a first length 2478 of about 2-inches; and the second portion 2480 may have a second length 2482 of about 4.9-inches.

In an embodiment, the first portion 2475 of the body 2405 may have a first inner diameter 2485 and a second inner diameter 2490.

In an embodiment, the first inner diameter **2485** of the first portion **2475** may have any suitable diameter. In an embodiment, the first inner diameter **2485** of the first portion **2475** may be from about 3-inches to about 5-inches, and any range or value there between. In an embodiment, the first inner diameter **2485** of the first portion **2475** may be about 3.9-inches.

In an embodiment, the second inner diameter **2490** of the first portion **2475** may have any suitable diameter. In an embodiment, the second inner diameter **2490** of the first portion **2475** may be from about 2-inches to about 5-inches, and any range or value there between. In an embodiment, the second inner diameter **2490** of the first portion **2475** may be about 3-inches.

In an embodiment, an outer surface of the first portion **2475** and an inner surface of the first portion **2475** form an angle **2495** over a third length **24125**. In an embodiment, the angle may be from about 10-degrees to about 20-degrees, and any range or value there between. In an embodiment, the angle **2495** may be about 15-degrees.

In an embodiment, the third length **24125** may be from about 1-inch to about 2-inches, and any range or value there between. In an embodiment, the third length **24125** may be about 1.5-inches.

Optional First End Retaining Ring

FIG. 25 illustrates a detailed, cross-sectional view of the optional drilling mud screen **2500**, showing an optional first end retaining ring **25110**. As shown in FIG. 25, the optional drilling mud screen **2500** has a body **2505**, a drilling mud outlet **2525**, a filter **2530**, an outer surface of body **2595** and an optional first end retaining ring **25110**.

As shown in FIGS. 22B and 25, the filter **2230** may be held together with an optional first end retaining ring **25110**. In an embodiment, the optional filter retaining ring **25110** may have a plurality of holes to hold the plurality of rods to form the filter **2230**. In an embodiment, the plurality of rods may be connected to the plurality of holes in the optional filter retainer ring via a connection. Any suitable connection may be used for the filter **2230** and first end retaining ring **25110**. For example, suitable connections include, but are not limited to, welds. Connections are well known in the art. In an embodiment, the plurality of rods may be connected to the plurality of holes in the retainer ring via a weld.

In an embodiment, the optional first end retaining ring **25110** of the optional drilling mud screen **2500** may be constructed of any suitable material. For example, suitable materials include, but are not limited to, any alloy steel or tool steel. In an embodiment, the optional first end retaining ring **25110** may be constructed of an AISI 4145 or equivalent material. See e.g., FIGS. 5A-5E. In an embodiment, the optional first end retaining ring **25110** may be constructed of D2 tool steel or equivalent material.

In an embodiment, the optional first end retaining ring **25110** of the optional drilling mud screen **2500** may have a hardened coating to reduce washing (i.e., erosion) of the retaining ring **25110**. For example, suitable hardened coatings include, but are not limited to, any Carbide coating or equivalent. In an embodiment, the optional first end retaining ring **25110** may have a Carbide coating with about 6% Cobalt binder or equivalent material.

In an embodiment, the optional first end retaining ring **25110** may be modified to reduce an inside surface exit angle between the first portion **2575** and the second portion **2580** of the drilling mud screen **2500**, resulting in increased flow efficiency and decreased erosion. In an embodiment, the exit angle may be about 10-degrees to about 90-degrees, and any range or value there between. In an embodiment, the exit

angle may be from about 10-degrees to about 50-degrees. In an embodiment, the exit angle may be about 30-degrees.

Optional Filter Retaining Ring

FIG. 26A illustrates a side view of an optional drilling mud screen system **2600** according to an embodiment of the present invention, showing an optional filter length **26115**, and an optional filter retaining ring **26120**; and FIG. 26B illustrates a detailed, cross-sectional view of the optional drilling mud screen system **2600** of FIG. 26A, showing an optional drilling mud screen insert **26105**, an optional filter length **26115**, and an optional filter retaining ring **26120**. As shown in FIGS. 26A and 26B, the optional drilling mud screen system **2600** has an optional drilling mud screen insert **26105**, an optional filter length **26115**, and an optional retaining ring **26120**.

In an embodiment, the optional filter retaining ring **26120** of the optional drilling mud screen **2640** may be constructed of any suitable material. For example, suitable materials include, but are not limited to, any alloy steel or tool steel.

In an embodiment, the optional filter retaining ring **26120** may be constructed of an AISI 4145 or equivalent material. See e.g., FIGS. 5A-5E. In an embodiment, the optional filter retaining ring **26120** may be constructed of D2 tool steel or equivalent material.

In an embodiment, the optional filter retaining ring **26120** of the optional drilling mud screen **2640** may have a hardened coating to reduce washing (i.e., erosion) of the optional filter retaining ring **26120**. For example, suitable hardened coatings include, but are not limited to, any Carbide coating or equivalent. In an embodiment, the optional filter retaining ring **26120** may have a Carbide coating with about 6% Cobalt binder or equivalent material.

In an embodiment, the optional filter retaining ring **26120** of the optional drilling mud screen **2640** may be modified to reduce inside surface entry and exit angles of the drilling mud screen **2640**, resulting in increased flow efficiency and decreased erosion. In an embodiment, the exit and entry angles may be from about 10-degrees to about 90-degrees, and any range or value there between. In an embodiment, the entry and exit angles may be from about 10-degrees to about 50-degrees. In an embodiment, the entry and exit angles may be about 30-degrees.

FIG. 27A illustrates an end view of an optional filter retaining ring **2700** according to an embodiment of the present invention; FIG. 27B illustrates a detailed, cross-sectional view of A-A of FIG. 27A; and FIG. 27C illustrates a detailed, cross-sectional view of B of FIG. 27B.

As shown in FIGS. 22B and 27A, the filter **2230** may be held together with an optional filter retaining ring **2700**. In an embodiment, the optional filter retaining ring **2700** may have a plurality of holes **2705** to hold the plurality of rods to form the filter **2230**. In an embodiment, the plurality of rods may be connected to the plurality of holes in the optional filter retainer ring via a connection. Any suitable connection may be used for the filter **2230** and filter retaining ring **2700**. For example, suitable connections include, but are not limited to, welds. Connections are well known in the art. In an embodiment, the plurality of rods may be connected to the plurality of holes in the retainer ring via a weld.

In an embodiment, the optional filter retaining rings **2700** of the optional drilling mud screen **2200** may be constructed of any suitable material. For example, suitable materials include, but are not limited to, any alloy steel or tool steel. In an embodiment, the optional filter retaining rings **2700** may be constructed of 304 stainless steel material. See e.g., FIGS. 5A & 5E. In an embodiment, the optional filter

retaining rings 2700 may be constructed of AISI 4145 or equivalent material. In an embodiment, the optional filter retaining rings 2700 may be constructed of D2 tool steel or equivalent material.

In an embodiment, the optional filter retaining ring 2700 of the optional drilling mud screen 2220 may have a hardened coating to reduce washing (i.e., erosion) of the screen 2200. For example, suitable hardened coatings include, but are not limited to, any Carbide coating or equivalent. In an embodiment, the optional filter retaining rings 2700 may have a Carbide coating with about 6% Cobalt binder or equivalent material.

In an embodiment, the optional filter retaining ring 2700 of the optional drilling mud screen 2200 may be modified to reduce inside surface entry and exit angles of the drilling mud screen 2200, resulting in increased flow efficiency and decreased erosion. In an embodiment, the entry and exit angles may be from about 10-degrees to about 50-degrees, and any range or value there between. In an embodiment, the entry and exit angles may be about 25-degrees or about 30-degrees.

Optional Filter Length

FIG. 26A illustrates a side view of an optional drilling mud screen system 2600 according to an embodiment of the present invention, showing an optional filter length 2615, and an optional filter retaining ring 26120; and FIG. 26B illustrates a detailed, cross-sectional view of the optional drilling mud screen system 2600 of FIG. 26A, showing an optional drilling mud screen insert 26105, an optional filter length 26115, and an optional filter retaining ring 26120. As shown in FIGS. 26A and 26B, the optional drilling mud screen system 2600 has an optional drilling mud screen insert 26105, an optional filter length 26115, and an optional retaining ring 26120.

As shown in FIG. 26B, the optional drilling mud screen 2640 has a first portion 2675 and a second portion 2680. In an embodiment, the first portion 2675 of the optional drilling mud screen 2640 has a first length 26125; and the second portion 2680 of the optional drilling mud screen 2640 has a second length 26130. The first portion 2675 and the second portion 2680 may be any suitable length. In an embodiment, the first portion 2675 may have a first length 26125 from about 6-inches to about 10-inches, and any range or value there between; and the second portion 2680 may have a second length 26130 from about 14-inches to about 20-inches, and any range or value there between. In an embodiment, the first portion 2275 may have a first length 26125 of about 7.5-inches; and the second portion 2680 may have a second length 26130 of about 17.5-inches.

In an embodiment, the second portion 2680 of the optional drilling mud screen 2640 has a first section 26135, a second section 26145 and a third section 26155. In an embodiment, the first section 26135 has a third length 26140, the second section 26145 has a fourth length 26150 and the third section 26155 has a fifth length 26160. The first section 26135, the second section 26145 and the third section 26155 may be any suitable length. In an embodiment, the first section 26135 of the optional drilling mud screen 2640 may be up to about 20-25% longer than the second section 26145 and/or the third section 26155, resulting in increased flow efficiency and decreased erosion.

In an embodiment, the first section 26135 may have a third length 26140 from about 4-inches to about 8-inches, and any range or value there between. In an embodiment, the first section 26135 may have a third length 26140 of about 6-inches.

In an embodiment, the second section 26145 may have a fourth length 26150 from about 4-inches to about 8-inches, and any range or value there between. In an embodiment, the second section 26145 may have a fourth length 26150 of about 5-inches.

In an embodiment, the third section 26155 may have a fifth length 26160 from about 4-inches to about 8-inches, and any range or value there between. In an embodiment, the third section 26155 may have a fifth length 26160 of about 5-inches.

Optional Cementing Configuration

FIG. 28 illustrates a cross-sectional view of a drilling mud screen system in a cementing configuration 2800 according to an embodiment of the present invention, showing an optional first transducer subassembly 28100' having an optional transducer 28105, an optional gate valve 28205 and an optional second transducer subassembly 28100" having an optional low torque plug valve 28110. As shown in FIG. 28, the drilling mud screen system in a cementing configuration 2800 comprises an optional first transducer subassembly 28100' having an optional transducer 28105, a drilling mud screen system 28200, an optional gate valve 28300 and an optional second transducer subassembly 28100" having an optional low torque plug valve 28110.

In an embodiment, a first drilling mud inlet 28120' of the optional first transducer subassembly 28100' may be fluidly connected to, for example, an outlet of a drilling mud pump via a connection; and a first drilling mud outlet 28125' of the optional first transducer subassembly 28100' may be fluidly connected to, for example, a drilling mud inlet 28120 of a drilling mud screen system 28200 via a connection. Any suitable connection may be used for the first drilling mud inlet 28120' and the first drilling mud outlet 28125'. For example, suitable connections include, but are not limited to, pipe fittings and welds. Connections are well known in the art. In an embodiment, the first drilling mud inlet 28120' of the optional first transducer subassembly 28100' may be fluidly connected to, for example, an outlet of a drilling mud pump via a weld; and the first drilling mud outlet 28125' of the optional first transducer subassembly 28100' may be fluidly connected to a drilling mud inlet 28220 of a drilling mud screen system 28200 via a weld.

The inlet pressure to the first drilling mud inlet 28120' of the optional first transducer subassembly 28100' may be any suitable pressure. In an embodiment, the inlet pressure may be from about 7500 psi to about 10,000 psi, and any range or value there between.

In an embodiment, the transducer access port 28130 of the optional first transducer subassembly 28100' may be closed with an optional transducer 28105 via a fitting. Any suitable type of transducer 28105 may be used. For example, suitable types of transducers include, but are not limited to, displacement transducers, flow rate transducers, pressure transducers, temperature transducers and any combination thereof. Any suitable fitting may be used. For example, suitable fittings include, but are not limited to, pipe fittings. Fittings are well known in the art. In an embodiment, the transducer access port 2030 of the optional transducer subassembly 2000 may be closed with, for example, a pressure transducer 28105 via a 2-inch 1502 WECO union.

In an embodiment, a computing device (such as a rig computer) may include a bus that directly or indirectly couples the following devices: memory, one or more processors, one or more presentation components, one or more input/output (I/O) ports, I/O components, a user interface and a power supply. The computing device may include a variety of computer-readable media. The memory may

101

include computer-storage media in the form of volatile and/or nonvolatile memory. The presentation component(s) present data indications to a user or other device. The user interface allows the user to input/output information to/from the computing device. The one or more I/O ports may allow the computing device to be logically coupled to other devices including a transducer 28105, and other I/O components, some of which may be built in. See e.g., FIG. 28. Examples of other I/O components include a printer, scanner, wireless device, and the like.

In an embodiment, pressure information from, for example, a pressure transducer 28105 will allow a driller to know when a drilling mud screen (not shown) in a drilling mud screen system 28200 is "packing off." For example, the pressure information from the pressure transducer 28105 at the drilling mud inlet 28220 of the drilling mud screen system 28200 may be compared to, for example, pressure information from a pressure transducer on a pressure transducer for a stand pipe. If the pressure decreases at the stand pipe and the pressure increases at the drilling mud inlet 28220 of the drilling mud screen system 28200, the drilling mud screen (not shown) is likely "packing off." If the pressure decreases or increases at both the stand pipe and the drilling mud screen system, then the problem is likely down hole and not at the drilling mud screen system 28200. If the problem is at the drilling mud screen system 28200, the drilling mud screen may be cleaned, repaired or replaced.

In an embodiment, a drilling mud inlet 28220 of the drilling mud screen system 28200 may be fluidly connected to, for example, a first drilling mud outlet 28125' of the optional first transducer subassembly 28100' via a connection; and a drilling mud outlet 28225 of the drilling mud screen system 28200 may be fluidly connected to, for example, a drilling mud inlet 28320 of an optional gate valve 28300 via a connection. Any suitable connection may be used for the drilling mud inlet 2820 and the drilling mud outlet 2825. For example, suitable connections include, but are not limited to, pipe fittings and welds. Connections are well known in the art. In an embodiment, the drilling mud inlet 28200 of the drilling mud screen system 28200 may be fluidly connected to, for example, a first drilling mud outlet 28120' of the optional first transducer subassembly 28100' via a weld; and the drilling mud outlet 28225 of the drilling mud screen system 28200 may be fluidly connected to, for example, a drilling mud inlet 28320 of the optional gate valve 28300 via a weld.

The inlet pressure to the drilling mud inlet 28220 of the drilling mud screen system 28200 may be any suitable pressure. In an embodiment, the inlet pressure may be from about 7500 psi to about 10,000 psi, and any range or value there between.

In an embodiment, a drilling mud inlet 28320 of the optional gate valve 28300 may be fluidly connected to, for example, a drilling mud outlet 28220 of the drilling mud screen system 28200 via a connection; and a drilling mud outlet 28325 of the optional gate valve 28300 may be fluidly connected to, for example, a second drilling mud inlet 28120" of the optional second transducer subassembly 28100" via a connection. Any suitable connection may be used for the drilling mud inlet 28320 and the drilling mud outlet 28325. For example, suitable connections include, but are not limited to, pipe fittings and welds. Connections are well known in the art. In an embodiment, the drilling mud inlet 28320 of the optional gate valve 28300 may be fluidly connected to, for example, a drilling mud outlet 28220 of a drilling mud screen system 28200 via a weld; and the drilling mud outlet 28225 of the optional gate valve 28300

102

may be fluidly connected to, for example, a second drilling mud inlet 28125" of the optional second transducer subassembly 28100" via a weld.

In an embodiment, a second drilling mud inlet 28120" of the optional second transducer subassembly 28100" may be fluidly connected to, for example, a drilling mud outlet 28325 of the optional gate valve 28300 via a connection; and a second drilling mud outlet 28125" of the optional second transducer subassembly 28100" may be fluidly connected to, for example, an inlet of a vibrator hose via a connection. Any suitable connection may be used for the second drilling mud inlet 28120" and the second drilling mud outlet 28125". For example, suitable connections include, but are not limited to, pipe fittings and welds. Connections are well known in the art. In an embodiment, a second drilling mud inlet 28120" of the optional second transducer subassembly 28100" may be fluidly connected to, for example, a drilling mud outlet 28325 of the optional gate valve 28300 via a weld; and a second drilling mud outlet 28125" of the optional second transducer subassembly 28100" may be fluidly connected to, for example, an inlet of a vibrator hose via a weld.

In an embodiment, an operator may close an optional gate valve 28300 to isolate a drilling mud screen system 28200 (and an upstream drilling mud pump) from cement for a cementing application. The operator may pump cement through an optional low torque plug valve 28110 in an optional second transducer assembly 28100", through a vibrator hose, through a stand pipe, through a top drive and through a casing running tool (CRT).

30 Optional Flow Loop Configuration

In an embodiment, one or more drilling mud screen systems may be used in an optional flow loop configuration to create a redundancy and/or to increase through put.

FIG. 36 illustrates a cross-sectional view of a drilling mud screen system in an optional flow loop configuration 3600 according to an embodiment of the present invention, showing a pair of drilling mud screen systems; and FIG. 37 illustrates an upper, right perspective view of the optional flow loop configuration 3700 of FIG. 36.

As shown in FIGS. 36 and 37, the flow loop configuration 3600, 3700 comprises a Y-connector (e.g., first drilling mud manifold) 3605, 3705 having a drilling mud inlet 3610, 3710 and a first drilling mud outlet 3615a, 3715a and a second drilling mud outlet 3615b, 3715b, a first gate valve 3620, 3720 having a first drilling mud inlet 3625, 3725 and a first drilling mud outlet 3630, 3730, a second gate valve 3635, 3735 having a second drilling mud inlet 3640, 3740 and a second drilling mud outlet 3645, 3745, a first spool 3650, 3750 having a first drilling mud inlet 3655, 3755 and a first drilling mud outlet 3660, 3760, a second spool 3665, 3765 having a second drilling mud inlet 3670, 3770 and a second drilling mud outlet 3675, 3775, a first drilling mud screen system 400, 600, 1400, 2100, 2300, 3680, 3780 having a first drilling mud inlet 420, 620a, 1420, 2120a, 2320a, 3685, 3785 and a first drilling mud outlet 425, 625b, 1425, 2120b, 3690, 3790, a second drilling mud screen system 400, 600, 1400, 2100, 2300, 3695, 3795 having a second drilling mud inlet 420, 620a, 1420, 2120a, 2320a, 36100, 37100 and a second drilling mud outlet 425, 625b, 1425, 2125b, 2325b, 36105, 37105, a first L-connector 36110, 37110 having a first drilling mud inlet 36115, 37115 and a first drilling mud outlet 36120, 37120, a second L-connector 36125, 37125 having a second drilling mud inlet 36130, 37130 and a second drilling mud outlet 36135, 37135, a third gate valve 36140, 37140 having a third drilling mud inlet 36145, 37145 and a third drilling mud outlet 36150, 37150, a fourth gate valve 36155, 37155 having a fourth drilling mud inlet

36160, 37160 and a fourth drilling mud outlet 36165, 37165, and a T-connector (e.g., second drilling mud manifold) 36170, 37170 having a first drilling mud inlet 36175, 37175, a second drilling mud inlet 36180, 37180 and a drilling mud outlet 36185, 37185.

In an embodiment, the drilling mud inlet 3610, 3710 may be fluidly connected to, for example, an outlet of a drilling mud pump via a connection; and the drilling mud outlet 36185, 37185 may be fluidly connected to an inlet of a vibrator hose via a connection. Any suitable connection may be used for the drilling mud inlet 3610, 3710 and drilling mud outlet 36185, 37185. For example, suitable connections include, but are not limited to, pipe fittings and welds. Connections are well known in the art. In an embodiment, the drilling mud inlet 3610, 3710 may be fluidly connected to, for example, an outlet of a drilling mud pump via a weld; and the drilling mud outlet 36185, 37185 may be fluidly connected to an inlet of a vibrator hose via a weld.

In an embodiment, the flow loop configuration 3600, 3700 comprises a first stub connection 36210 from, for example, an outlet of a drilling mud pump to a drilling mud inlet 3610, 3710 of a Y-connector (e.g., first drilling mud manifold) 3605, 3705.

In an embodiment, the flow loop configuration 3600, 3700 comprises a second stub connection 36215 from, for example, a drilling mud outlet 36185, 37185 of a T-connector (e.g., second drilling mud manifold) 36170, 37170 to an inlet of a vibrator hose.

In an embodiment, the first drilling mud outlet 3615a, 3715a of the Y-connector (e.g., first drilling mud manifold) 3605, 3705 and the first gate valve 3620, 3720 may be fluidly connected by a connection. Any suitable connection may be used for the first drilling mud outlet 3615a, 3715a of the Y-connector 3605, 3705 and the first gate valve 3620, 3720. For example, suitable connections include, but are not limited to, flanges and pipe fittings. Connections are well known in the art.

In an embodiment, the Y-connector (e.g., first drilling mud manifold) 3605, 3705 may have an integral flange at the first drilling mud outlet 3615a, 3715a.

In an embodiment, the first gate valve 3620, 3720 may have an integral flange at the first drilling mud inlet 3625, 3725 and/or the first drilling mud outlet 3630, 3730.

In an embodiment, the second drilling mud outlet 3615b, 3715b of the Y-connector (e.g., first drilling mud manifold) 3605, 3705 and the second gate valve 3635, 3735 may be fluidly connected by a connection. Any suitable connection may be used for the second drilling mud outlet 3615b, 3715b of the Y-connector (e.g., first drilling mud manifold) 3605, 3705 and the second gate valve 3635, 3735. For example, suitable connections include, but are not limited to, flanges and pipe fittings. Connections are well known in the art.

In an embodiment, the Y-connector (e.g., first drilling mud manifold) 3605, 3705 may have an integral flange at the second drilling mud outlet 3615b, 3715b.

In an embodiment, the second gate valve 3635, 3735 may have an integral flange at the second drilling mud inlet 3640, 3740 and/or the second drilling mud outlet 3645, 3745.

In an embodiment, the first drilling mud outlet 3630, 3730 of the first gate valve 3620, 3720 and the first spool 3650, 3750 may be fluidly connected by a connection. Any suitable connection may be used for the first drilling mud outlet 3630, 3730 of the first gate valve 3620, 3720 and the first spool 3650, 3750. For example, suitable connections include, but are not limited to, flanges and pipe fittings. Connections are well known in the art.

In an embodiment, the first gate valve 3620, 3720 may have an integral flange at the first drilling mud inlet 3625, 3725 and/or the first drilling mud outlet 3630, 3730.

In an embodiment, the first spool 3650, 3750 may have an integral flange at the first drilling mud inlet 3655, 3755 and/or the first drilling mud outlet 3660, 3760.

In an embodiment, the second drilling mud outlet 3645, 3745 of the second gate valve 3635, 3735 and the second spool 3665, 3765 may be fluidly connected by a connection. 10 Any suitable connection may be used for the second drilling mud outlet 3645, 3745 of the second gate valve 3635, 3735 and the second spool 3665, 3765. For example, suitable connections include, but are not limited to, flanges and pipe fittings. Connections are well known in the art.

15 In an embodiment, the second gate valve 3635, 3735 may have an integral flange at the second drilling mud inlet 3640, 3740 and/or the second drilling mud outlet 3645, 3745.

In an embodiment, the second spool 3665, 3765 may have an integral flange at the second drilling mud inlet 3670, 3770 20 and/or the second drilling mud outlet 3675, 3775.

In an embodiment, the first drilling mud outlet 3645, 3745 of the first spool 3635, 3735 and the first drilling mud inlet 420, 620a, 1420, 2120a, 2320a, 3685, 3785 of the first drilling mud screen system 400, 600, 1400, 2100, 2300, 3680, 3780 may be fluidly connected by a connection. Any suitable connection may be used for the first drilling mud outlet 3645, 3745 of the first spool 3635, 3735 and the first drilling mud inlet 420, 620a, 1420, 2120a, 2320a, 3685, 3785 of the first drilling mud screen system 400, 600, 1400, 2100, 2300, 3680, 3780. For example, suitable connections include, but are not limited to, flanges and pipe fittings. Connections are well known in the art.

30 In an embodiment, the first spool 3650, 3750 may have an integral flange at the first drilling mud inlet 3655, 3755 and/or the first drilling mud outlet 3660, 3760.

In an embodiment, the flow loop configuration 3600, 3700 comprises a first cross-over connection 3105, 36190, 37190 from a first spool 3650, 3750 to a first drilling mud screen system 400, 600, 1400, 2100, 2300, 3680, 3780.

40 In an embodiment, the first cross-over connection 3105, 36190, 37190 may have an integral flange at a first drilling mud inlet and/or a first drilling mud outlet.

In an embodiment, the second drilling mud outlet 3675, 3775 of the second spool 3665, 3765 and the second drilling mud inlet 420, 620a, 1420, 2120a, 2320a, 36100, 37100 of the second drilling mud screen system 400, 600, 1400, 2100, 2300, 3695, 3795 may be fluidly connected by a connection. Any suitable connection may be used for the second drilling mud outlet 3675, 3775 of the second spool 3665, 3765 and the second drilling mud inlet 420, 620a, 1420, 2120a, 2320a, 36100, 37100 of the second drilling mud screen system 400, 600, 1400, 2100, 2300, 3695, 3795. For example, suitable connections include, but are not limited to, flanges and pipe fittings. Connections are well known in the art.

55 In an embodiment, the second spool 3665, 3765 may have an integral flange at the second drilling mud inlet 3670, 3770 and/or the second drilling mud outlet 3675, 3775.

In an embodiment, the flow loop configuration 3600, 3700 60 comprises a second cross-over connection 3105, 36195, 37195 from a second spool 3665, 3765 to a second drilling mud screen system 400, 600, 1400, 2100, 2300, 3695, 3795.

In an embodiment, the second cross-over connection 3105, 36195, 37195 may have an integral flange at a second drilling mud inlet.

65 In an embodiment, the first drilling mud outlet 425, 625b, 1425, 2125b, 2325b, 3690, 3790 of the first drilling mud

105

screen system 400, 600, 1400, 2100, 2300, 3680, 3780 and the first drilling mud inlet 36115, 37115 of the first L-connector 36110, 37110 may be fluidly connected by a connection. Any suitable connection may be used for the first drilling mud outlet 425, 625b, 1425, 2125b, 2325b, 3690, 3790 of the first drilling mud screen system 400, 600, 1300, 2100, 2300, 3680, 3780 and the first drilling mud inlet 36115, 37115 of the first L-connector 36110, 37110. For example, suitable connections include, but are not limited to, flanges and pipe fittings. Connections are well known in the art.

In an embodiment, the flow loop configuration 3600, 3700 comprises a third cross-over connection 3105, 36200, 37200 from a first drilling mud screen system 400, 600, 1400, 2100, 2300, 3680, 3780 to a first L-connector 36110, 37110.

In an embodiment, the third cross-over connection 3105, 36200, 37200 may have an integral flange at a third drilling mud inlet and/or a third drilling mud outlet.

In an embodiment, the first L-connector 36110, 37110 may have an integral flange at the first drilling mud inlet 36115, 37115 and/or the first drilling mud outlet 36120, 37120.

In an embodiment, the second drilling mud outlet 425, 625b, 1425, 2125b, 2325b, 36105, 37105 of the second drilling mud screen system 400, 600, 1400, 2100, 2300, 3695, 3795 and the second drilling mud inlet 36135, 37135 of the second L-connector 36125, 37125 may be fluidly connected by a connection. Any suitable connection may be used for the second drilling mud outlet 425, 625b, 1425, 2125b, 2325b, 36105, 37105 of the second drilling mud screen system 400, 600, 1300, 2100, 2300, 3695, 3795 and the second drilling mud inlet 36135, 37135 of the second L-connector 36125, 37125. For example, suitable connections include, but are not limited to, flanges and pipe fittings. Connections are well known in the art.

In an embodiment, the flow loop configuration 3600, 3700 comprises a fourth cross-over connection 3105, 36205, 37205 from a second drilling mud screen system 400, 600, 1400, 2100, 2300, 3695, 3795 to a second L-connector 36125, 37125.

In an embodiment, the fourth cross-over connection 3105, 36205, 37205 may have an integral flange at a fourth drilling mud inlet and/or a fourth drilling mud outlet.

In an embodiment, the second L-connector 36125, 37125 may have an integral flange at the second drilling mud inlet 36130, 37130 and/or the second drilling mud outlet 36135, 37135.

In an embodiment, the first drilling mud outlet 36120, 37120 of the first L-connector 36110, 37110 and the third drilling mud inlet 36145, 37145 of the third gate valve 36140, 37140 may be fluidly connected by a connection. Any suitable connection may be used for the first drilling mud outlet 36120, 37120 of the first L-connector 36110, 37110 and the third drilling mud inlet 36145, 37145 of the third gate valve 36140, 37140. For example, suitable connections include, but are not limited to, flanges and pipe fittings. Connections are well known in the art.

In an embodiment, the first L-connector 36110, 37110 may have an integral flange at the first drilling mud inlet 36115, 37115 and/or the first drilling mud outlet 36120, 37120.

In an embodiment, the third gate valve 36140, 37140 may have an integral flange at the third drilling mud inlet 36145, 37145 and/or the third drilling mud outlet 36150, 37150.

In an embodiment, the second drilling mud outlet 36135, 37135 of the second L-connector 36125, 37125 and the fourth drilling mud inlet 36160, 37160 of the fourth gate

106

valve 36155, 37155 may be fluidly connected by a connection. Any suitable connection may be used for the second drilling mud outlet 36135, 37135 of the second L-connector 36125, 37125 and the fourth drilling mud inlet 36160, 37160 of the fourth gate valve 36155, 37155. For example, suitable connections include, but are not limited to, flanges and pipe fittings. Connections are well known in the art.

In an embodiment, the second L-connector 36125, 37125 may have an integral flange at the second drilling mud inlet 36130, 37130 and/or the second drilling mud outlet 36135, 37135.

In an embodiment, the fourth gate valve 36155, 37155 may have an integral flange at the fourth drilling mud inlet 36160, 37160 and/or the fourth drilling mud outlet 36165, 37165.

In an embodiment, the third drilling mud outlet 36150, 37150 of the third gate valve 36140, 37140 and the first drilling mud inlet 36175, 37175 of the T-connector (e.g., second drilling mud manifold) 36170, 37170 may be fluidly connected by a connection. Any suitable connection may be used for the third drilling mud outlet 36150, 37150 of the third gate valve 36140, 37140 and the first drilling mud inlet 36175, 37175 of the T-connector (e.g., second drilling mud manifold) 36170, 37170. For example, suitable connections include, but are not limited to, flanges and pipe fittings. Connections are well known in the art.

In an embodiment, the third gate valve 36140, 37140 may have an integral flange at the third drilling mud inlet 36145, 37145 and/or the third drilling mud outlet 36150, 37150.

In an embodiment, the T-connector (e.g., second drilling mud manifold) 36170, 37170 may have an integral flange at the first drilling mud inlet 36175, 37175 and/or the second drilling mud inlet 36180, 37180.

In an embodiment, the fourth drilling mud outlet 36165, 37165 of the fourth gate valve 36155, 37155 and the second drilling mud inlet 36180, 37180 of the T-connector (e.g., second drilling mud manifold) 36170, 37170 may be fluidly connected by a connection. Any suitable connection may be used for the fourth drilling mud outlet 36165, 37165 of the fourth gate valve 36155, 37155 and the second drilling mud inlet 36180, 37180 of the T-connector (e.g., second drilling mud manifold) 36170, 37170. For example, suitable connections include, but are not limited to, flanges and pipe fittings. Connections are well known in the art.

In an embodiment, the fourth gate valve 36155, 37155 may have an integral flange at the fourth drilling mud inlet 36160, 37160 and/or the fourth drilling mud outlet 36165, 37165.

In an embodiment, the T-connector (e.g., second drilling mud manifold) 36170, 37170 may have an integral flange at the first drilling mud inlet 36175, 37175 and/or the second drilling mud inlet 36180, 37180.

Alternative Optional Flow Loop Configuration

In an embodiment, one or more piston-style drilling mud screen systems may be used in an alternative optional flow loop configuration to create a redundancy and/or to increase through put.

FIG. 38 illustrates a cross-sectional view of a drilling mud screen system in an alternative flow loop configuration 3800, showing four drilling mud screen systems.

As shown in FIG. 38, the alternative optional flow loop configuration 3800 comprises a first drilling mud manifold 3805 having a first drilling mud inlet 3810, a first, first drilling mud outlet 3815, a first, second drilling mud outlet 3820, a first, third drilling mud outlet 3825 and a first, fourth drilling mud outlet 3830, a first gate valve 3835 having a first drilling mud inlet 3840 and a first drilling mud outlet 3845,

a second gate valve **3850** having a second drilling mud inlet **3855** and a second drilling mud outlet **3860**, a third gate valve **3865** having a third drilling mud inlet **3870** and a third drilling mud outlet **3875**, a fourth gate valve **3880** having a fourth drilling mud inlet **3885** and a fourth drilling mud outlet **3890**, a first drilling mud screen system **3000, 3300, 3400, 3895** having a first drilling mud inlet **3020a, 3320a, 38100** and a first drilling mud outlet **3025b, 3325b, 38105**, a second drilling mud screen system **3000, 3300, 3400, 38110** having a second drilling mud inlet **3020a, 3320a, 38115** and a second drilling mud outlet **3025b, 3325b, 38120**, a third drilling mud screen system **3000, 3300, 3400, 38125** having a third drilling mud inlet **3020a, 3320a, 38130** and a third drilling mud outlet **3025b, 3325b, 38135**, a fourth drilling mud screen system **3000, 3300, 3400, 38140** having a fourth drilling mud inlet **3020a, 3320a, 38145** and a fourth drilling mud outlet **3025b, 3325b, 38150**, a fifth gate valve **38155** having a fifth drilling mud inlet **38160** and a fifth drilling mud outlet **38165**, a sixth gate valve **38170** having a sixth drilling mud inlet **38175** and a sixth drilling mud outlet **38180**, a seventh gate valve **38185** having a seventh drilling mud inlet **38190** and a seventh drilling mud outlet **38195**, an eighth gate valve **38200** having an eighth drilling mud inlet **38205** and an eighth drilling mud outlet **38210**, and a second drilling mud manifold **38215** having a second, first drilling mud inlet **38220**, a second, second drilling mud inlet **38225**, a second, third drilling mud inlet **38230**, a second, fourth drilling mud inlet **38235** and a second drilling mud outlet **38240**.

In an embodiment, the drilling mud inlet **3810** may be fluidly connected to, for example, an outlet of a drilling mud pump via a connection; and the drilling mud outlet **38240** may be fluidly connected to an inlet of a vibrator hose via a connection. Any suitable connection may be used for the drilling mud inlet **3810** and drilling mud outlet **38240**. For example, suitable connections include, but are not limited to, pipe fittings and welds. Connections are well known in the art. In an embodiment, the drilling mud inlet **3810** may be fluidly connected to, for example, an outlet of a drilling mud pump via a weld; and the drilling mud outlet **38240** may be fluidly connected to an inlet of a vibrator hose via a weld.

In an embodiment, the flow loop configuration **3800** comprises a first stub connection (not shown) from, for example, an outlet of a drilling mud pump to a first drilling mud inlet **3810** of a first drilling mud manifold **3805**. See e.g., FIG. 36.

In an embodiment, the flow loop configuration **3800** comprises a second stub connection (not shown) from, for example, a second drilling mud outlet **38240** of a second drilling mud manifold **38215** to an inlet of a vibrator hose. See e.g., FIG. 36.

In an embodiment, the first, first drilling mud outlet **3815** of the first drilling mud manifold **3805** and the first drilling mud inlet **3840** of the first gate valve **3835** may be fluidly connected by a connection. Any suitable connection may be used for the first, first drilling mud outlet **3815** of the first drilling mud manifold **3805** and the first drilling mud inlet **3840** of the first gate valve **3835**. For example, suitable connections include, but are not limited to, flanges and pipe fittings. Connections are well known in the art.

In an embodiment, the first drilling mud manifold **3805** may have an integral flange at the first, first drilling mud outlet **3815**, the first, second drilling mud outlet **3820**, the first, third drilling mud outlet **3825**, and the first, fourth drilling mud outlet **3830**.

In an embodiment, the first gate valve **3835** may have an integral flange at the first drilling mud inlet **3840** and/or the first drilling mud outlet **3845**.

In an embodiment, the first, first drilling mud outlet **3815** of the first drilling mud manifold **3805** may be fluidly connected to the first drilling mud inlet **3840** of the first gate valve **3835**. In an embodiment, the first, first drilling mud outlet **3815** of the first drilling mud manifold **3805** may be sealed to the first drilling mud inlet **3840** of the first gate valve **3835** via a gasket or an O-ring. Any suitable gasket or O-ring may be used. For example, suitable O-rings include, but are not limited to, 300 Series O-rings. Gaskets and O-rings are well known in the art.

In an embodiment, the first, second drilling mud outlet **3820** of the first drilling mud manifold **3805** and the second drilling mud inlet **3855** of the second gate valve **3850** may be fluidly connected by a connection. Any suitable connection may be used for the first, second drilling mud outlet **3820** of the first drilling mud manifold **3805** and the second drilling mud inlet **3855** of the second gate valve **3850**. For example, suitable connections include, but are not limited to, flanges and pipe fittings. Connections are well known in the art.

In an embodiment, the first drilling mud manifold **3805** may have an integral flange at the first, first drilling mud outlet **3815**, the first, second drilling mud outlet **3820**, the first, third drilling mud outlet **3825**, and the first, fourth drilling mud outlet **3830**.

In an embodiment, the second gate valve **3850** may have an integral flange at the second drilling mud inlet **3855** and/or the second drilling mud outlet **3860**.

In an embodiment, the first, second drilling mud outlet **3820** of the first drilling mud manifold **3805** may be fluidly connected to the second drilling mud inlet **3855** of the second gate valve **3850**. In an embodiment, the first, second drilling mud outlet **3820** of the first drilling mud manifold **3805** may be sealed to the second drilling mud inlet **3855** of the second gate valve **3850** via a gasket or an O-ring. Any suitable gasket or O-ring may be used. For example, suitable O-rings include, but are not limited to, 300 Series O-rings. Gaskets and O-rings are well known in the art.

In an embodiment, the first, third drilling mud outlet **3825** of the first drilling mud manifold **3805** and the third drilling mud inlet **3870** of the third gate valve **3865** may be fluidly connected by a connection. Any suitable connection may be used for the first, third drilling mud outlet **3825** of the first drilling mud manifold **3805** and the third drilling mud inlet **3870** of the third gate valve **3865**. For example, suitable connections include, but are not limited to, flanges and pipe fittings. Connections are well known in the art.

In an embodiment, the first drilling mud manifold **3805** may have an integral flange at the first, first drilling mud outlet **3815**, the first, second drilling mud outlet **3820**, the first, third drilling mud outlet **3825**, and the first, fourth drilling mud outlet **3830**.

In an embodiment, the third gate valve **3865** may have an integral flange at the third drilling mud inlet **3870** and/or the third drilling mud outlet **3875**.

In an embodiment, the first, third drilling mud outlet **3825** of the first drilling mud manifold **3805** may be fluidly connected to the third drilling mud inlet **3870** of the third gate valve **3865**. In an embodiment, the first, third drilling mud outlet **3825** of the first drilling mud manifold **3805** may be sealed to the third drilling mud inlet **3870** of the third gate valve **3865** via a gasket or an O-ring. Any suitable gasket or O-ring may be used. For example, suitable O-rings include,

109

but are not limited to, 300 Series O-rings. Gaskets and O-rings are well known in the art.

In an embodiment, the first, fourth drilling mud outlet **3830** of the first drilling mud manifold **3805** and the fourth drilling mud inlet **3885** of the fourth gate valve **3880** may be fluidly connected by a connection. Any suitable connection may be used for the first, fourth drilling mud outlet **3830** of the first drilling mud manifold **3805** and the fourth drilling mud inlet **3885** of the fourth gate valve **3880**. For example, suitable connections include, but are not limited to, flanges and pipe fittings. Connections are well known in the art.

In an embodiment, the first drilling mud manifold **3805** may have an integral flange at the first, first drilling mud outlet **3815**, the first, second drilling mud outlet **3820**, the first, third drilling mud outlet **3825**, and the first, fourth drilling mud outlet **3830**.

In an embodiment, the fourth gate valve **3880** may have an integral flange at the fourth drilling mud inlet **3885** and/or the fourth drilling mud outlet **3890**.

In an embodiment, the first, fourth drilling mud outlet **3830** of the first drilling mud manifold **3805** may be fluidly connected to the fourth drilling mud inlet **3885** of the fourth gate valve **3880**. In an embodiment, the first, fourth drilling mud outlet **3830** of the first drilling mud manifold **3805** may be sealed to the fourth drilling mud inlet **3885** of the fourth gate valve **3880** via a gasket or an O-ring. Any suitable gasket or O-ring may be used. For example, suitable O-rings include, but are not limited to, 300 Series O-rings. Gaskets and O-rings are well known in the art.

In an embodiment, the first drilling mud outlet **3845** of the first gate valve **3835** and the first drilling mud inlet **30020a, 33020a, 34020a, 38100** of the first drilling mud screen system **3000, 3300, 3400, 3895** may be fluidly connected by a connection. Any suitable connection may be used for the first drilling mud outlet **3845** of the first gate valve **3835** and the first drilling mud inlet **30020a, 33020a, 34020a, 38100** of the first drilling mud screen system **3000, 3300, 3400, 3895**. For example, suitable connections include, but are not limited to, flanges and pipe fittings. Connections are well known in the art.

In an embodiment, the first gate valve **3835** may have an integral flange at the first drilling mud inlet **3840** and/or the first drilling mud outlet **3845**.

In an embodiment, the flow loop configuration **3800** comprises a first cross-over connection **3105, 38245** from a first gate valve **3835** to a first drilling mud screen system **3000, 3300, 3400, 3895**.

In an embodiment, the first cross-over connection **3105, 38245** may have an integral flange at a first drilling mud inlet and/or first drilling mud outlet.

In an embodiment, the second drilling mud outlet **3860** of the second gate valve **3850** and the second drilling mud inlet **30020a, 33020a, 34020a, 38115** of the second drilling mud screen system **3000, 3300, 3400, 38110** may be fluidly connected by a connection. Any suitable connection may be used for the second drilling mud outlet **3860** of the second gate valve **3850** and the second drilling mud inlet **30020a, 33020a, 34020a, 38115** of the second drilling mud screen system **3000, 3300, 3400, 38110**. For example, suitable connections include, but are not limited to, flanges and pipe fittings. Connections are well known in the art.

In an embodiment, the second gate valve **3850** may have an integral flange at the second drilling mud inlet **3855** and/or the second drilling mud outlet **3860**.

In an embodiment, the flow loop configuration **3800** comprises a second cross-over connection **3105, 38250** from

110

a second gate valve **3850** to a second drilling mud screen system **3000, 3300, 3400, 38110**.

In an embodiment, the second cross-over connection **3105, 38250** may have an integral flange at a second drilling mud inlet.

In an embodiment, the third drilling mud outlet **3875** of the third gate valve **3865** and the third drilling mud inlet **30020a, 33020a, 34020a, 38130** of the third drilling mud screen system **3000, 3300, 3400, 38125** may be fluidly connected by a connection. Any suitable connection may be used for the third drilling mud outlet **3875** of the third gate valve **3865** and the third drilling mud inlet **30020a, 33020a, 34020a, 38130** of the third drilling mud screen system **3000, 3300, 3400, 38125**. For example, suitable connections include, but are not limited to, flanges and pipe fittings. Connections are well known in the art.

In an embodiment, the third gate valve **3865** may have an integral flange at the third drilling mud inlet **3870** and/or the third drilling mud outlet **3875**.

In an embodiment, the flow loop configuration **3800** comprises a third cross-over connection **3105, 38255** from a third gate valve **3865** to a third drilling mud screen system **3000, 3300, 3400, 38125**.

In an embodiment, the third cross-over connection **3105, 38255** may have an integral flange at a third drilling mud inlet and/or a third drilling mud outlet.

In an embodiment, the fourth drilling mud outlet **3890** of the fourth gate valve **3880** and the fourth drilling mud inlet **30020a, 33020a, 34020a, 38145** of the fourth drilling mud screen system **3000, 3300, 3400, 38140** may be fluidly connected by a connection. Any suitable connection may be used for the fourth drilling mud outlet **3890** of the fourth gate valve **3880** and the fourth drilling mud inlet **30020a, 33020a, 34020a, 38145** of the fourth drilling mud screen system **3000, 3300, 3400, 38140**. For example, suitable connections include, but are not limited to, flanges and pipe fittings. Connections are well known in the art.

In an embodiment, the fourth gate valve **3880** may have an integral flange at the fourth drilling mud inlet **3885** and/or the fourth drilling mud outlet **3890**.

In an embodiment, the flow loop configuration **3800** comprises a fourth cross-over connection **3105, 38260** from a fourth gate valve **3880** to a fourth drilling mud screen system **3000, 3300, 3400, 38140**.

In an embodiment, the fourth cross-over connection **3105, 38260** may have an integral flange at a fourth drilling mud inlet and/or a fourth drilling mud outlet.

In an embodiment, the first drilling mud outlet **30025b, 330025b, 34025b, 38105** of the first drilling mud screen system **3000, 3300, 3400, 3895** and the fifth drilling mud inlet **38160** of the fifth gate valve **38155** may be fluidly connected by a connection. Any suitable connection may be used for the first drilling mud outlet **30025b, 330025b, 34025b, 38105** of the first drilling mud screen system **3000, 3300, 3400, 3895** and the fifth drilling mud inlet **38160** of the fifth gate valve **38155**. For example, suitable connections include, but are not limited to, flanges and pipe fittings. Connections are well known in the art.

In an embodiment, the flow loop configuration **3800** comprises a fifth cross-over connection **3105, 38265** from a first drilling mud screen system **3000, 3300, 3400, 3895** to a fifth gate valve **38155**.

In an embodiment, the fifth cross-over connection **3105, 38265** may have an integral flange at a fifth drilling mud inlet and/or a fifth drilling mud outlet.

111

In an embodiment, the fifth gate valve **38155** may have an integral flange at the fifth drilling mud inlet **38160** and/or the fifth drilling mud outlet **38165**.

In an embodiment, the second drilling mud outlet **30025b**, **330025b**, **34025b**, **38120** of the second drilling mud screen system **3000**, **3300**, **3400**, **38110** and the sixth drilling mud inlet **38175** of the sixth gate valve **38170** may be fluidly connected by a connection. Any suitable connection may be used for the second drilling mud outlet **30025b**, **33025b**, **34025b**, **38120** of the second drilling mud screen system **3000**, **3300**, **3400**, **38110** and the sixth drilling mud inlet **38175** of the sixth gate valve **38170**. For example, suitable connections include, but are not limited to, flanges and pipe fittings. Connections are well known in the art.

In an embodiment, the flow loop configuration **3800** comprises a sixth cross-over connection **3105**, **38270** from a second drilling mud screen system **3000**, **3300**, **3400**, **38110** to a sixth gate valve **38170**.

In an embodiment, the sixth cross-over connection **3105**, **38270** may have an integral flange at a sixth drilling mud inlet and/or a sixth drilling mud outlet.

In an embodiment, the sixth gate valve **38170** may have an integral flange at the sixth drilling mud inlet **38175** and/or the sixth drilling mud outlet **38180**.

In an embodiment, the third drilling mud outlet **30025b**, **330025b**, **34025b**, **38135** of the third drilling mud screen system **3000**, **3300**, **3400**, **38125** and the seventh drilling mud inlet **38190** of the seventh gate valve **38185** may be fluidly connected by a connection. Any suitable connection may be used for the third drilling mud outlet **30025b**, **33025b**, **34025b**, **38135** of the third drilling mud screen system **3000**, **3300**, **3400**, **38125** and the seventh drilling mud inlet **38190** of the seventh gate valve **38185**. For example, suitable connections include, but are not limited to, flanges and pipe fittings. Connections are well known in the art.

In an embodiment, the flow loop configuration **3800** comprises a seventh cross-over connection **3105**, **38275** from a third drilling mud screen system **3000**, **3300**, **3400**, **38125** to a seventh gate valve **38185**.

In an embodiment, the seventh cross-over connection **3105**, **38275** may have an integral flange at a seventh drilling mud inlet and/or a seventh drilling mud outlet.

In an embodiment, the seventh gate valve **38185** may have an integral flange at the seventh drilling mud inlet **38190** and/or the seventh drilling mud outlet **38195**.

In an embodiment, the fourth drilling mud outlet **30025b**, **330025b**, **34025b**, **38150** of the fourth drilling mud screen system **3000**, **3300**, **3400**, **38140** and the eighth drilling mud inlet **38205** of the eighth gate valve **38200** may be fluidly connected by a connection. Any suitable connection may be used for the fourth drilling mud outlet **30025b**, **33025b**, **34025b**, **38150** of the fourth drilling mud screen system **3000**, **3300**, **3400**, **38140** and the eighth drilling mud inlet **38205** of the eighth gate valve **38200**. For example, suitable connections include, but are not limited to, flanges and pipe fittings. Connections are well known in the art.

In an embodiment, the flow loop configuration **3800** comprises an eighth cross-over connection **3105**, **38280** from a fourth drilling mud screen system **3000**, **3300**, **3400**, **38140** to an eighth gate valve **38200**.

In an embodiment, the eighth cross-over connection **3105**, **38280** may have an integral flange at an eighth drilling mud inlet and/or an eighth drilling mud outlet.

In an embodiment, the eighth gate valve **38200** may have an integral flange at the eighth drilling mud inlet **38205** and/or the eighth drilling mud outlet **38210**.

112

In an embodiment, the fifth drilling mud outlet **38165** of the fifth gate valve **38155** and the second, first drilling mud inlet **38220** of the second drilling mud manifold **38215** may be fluidly connected by a connection. Any suitable connection may be used for the fifth drilling mud outlet **38165** of the fifth gate valve **38155** and the second, first drilling mud inlet **38220** of the second drilling mud manifold **38215**. For example, suitable connections include, but are not limited to, flanges and pipe fittings. Connections are well known in the art.

In an embodiment, the fifth gate valve **38155** may have an integral flange at the fifth drilling mud inlet **38160** and/or the fifth drilling mud outlet **38165**.

In an embodiment, the second drilling mud manifold **38215** may have an integral flange at the second, first drilling mud outlet **38220**, the second, second drilling mud outlet **38225**, the second, third drilling mud outlet **38230**, and the second, fourth drilling mud outlet **38235**.

In an embodiment, the fifth drilling mud outlet **38165** of the fifth gate valve **38155** may be fluidly connected to the second, first drilling mud inlet **38220** of the second drilling mud manifold **38215**. In an embodiment, the fifth drilling mud outlet **38165** of the fifth gate valve **38155** may be sealed to the second, first drilling mud inlet **38220** of the second drilling mud manifold **38215** via a gasket or an O-ring. Any suitable gasket or O-ring may be used. For example, suitable O-rings include, but are not limited to, 300 Series O-rings. Gaskets and O-rings are well known in the art.

In an embodiment, the sixth drilling mud outlet **38180** of the sixth gate valve **38170** and the second, second drilling mud inlet **38225** of the second drilling mud manifold **38215** may be fluidly connected by a connection. Any suitable connection may be used for the sixth drilling mud outlet **38180** of the sixth gate valve **38170** and the second, second drilling mud inlet **38225** of the second drilling mud manifold **38215**. For example, suitable connections include, but are not limited to, flanges and pipe fittings. Connections are well known in the art.

In an embodiment, the sixth gate valve **38170** may have an integral flange at the sixth drilling mud inlet **38175** and/or the sixth drilling mud outlet **38180**.

In an embodiment, the second drilling mud manifold **38215** may have an integral flange at the second, first drilling mud outlet **38220**, the second, second drilling mud outlet **38225**, the second, third drilling mud outlet **38230**, and the second, fourth drilling mud outlet **38235**.

In an embodiment, the sixth drilling mud outlet **38180** of the sixth gate valve **38170** may be fluidly connected to the second, second drilling mud inlet **38225** of the second drilling mud manifold **38215**. In an embodiment, the sixth drilling mud outlet **38180** of the sixth gate valve **38170** may be sealed to the second, second drilling mud inlet **38225** of the second drilling mud manifold **38215** via a gasket or an O-ring. Any suitable gasket or O-ring may be used. For example, suitable O-rings include, but are not limited to, 300 Series O-rings. Gaskets and O-rings are well known in the art.

In an embodiment, the seventh drilling mud outlet **38195** of the seventh gate valve **38185** and the second, third drilling mud inlet **38230** of the second drilling mud manifold **38215** may be fluidly connected by a connection. Any suitable connection may be used for the seventh drilling mud outlet **38195** of the seventh gate valve **38185** and the second, third drilling mud inlet **38230** of the second drilling mud manifold **38215**. For example, suitable connections include, but are not limited to, flanges and pipe fittings. Connections are well known in the art.

In an embodiment, the seventh gate valve 38185 may have an integral flange at the seventh drilling mud inlet 38190 and/or the seventh drilling mud outlet 38195.

In an embodiment, the second drilling mud manifold 38215 may have an integral flange at the second, first drilling mud outlet 38220, the second, second drilling mud outlet 38225, the second, third drilling mud outlet 38230, and the second, fourth drilling mud outlet 38235.

In an embodiment, the seventh drilling mud outlet 38195 of the seventh gate valve 38185 may be fluidly connected to the second, third drilling mud inlet 38230 of the second drilling mud manifold 38215. In an embodiment, the seventh drilling mud outlet 38195 of the seventh gate valve 38185 may be sealed to the second, third drilling mud inlet 38230 of the second drilling mud manifold 38215 via a gasket or an O-ring. Any suitable gasket or O-ring may be used. For example, suitable O-rings include, but are not limited to, 300 Series O-rings. Gaskets and O-rings are well known in the art.

In an embodiment, the eighth drilling mud outlet 38210 of the eighth gate valve 38200 and the second, fourth drilling mud inlet 38235 of the second drilling mud manifold 38215 may be fluidly connected by a connection. Any suitable connection may be used for the eighth drilling mud outlet 38210 of the eighth gate valve 38200 and the second, fourth drilling mud inlet 38235 of the second drilling mud manifold 38215. For example, suitable connections include, but are not limited to, flanges and pipe fittings. Connections are well known in the art.

In an embodiment, the eighth gate valve 38200 may have an integral flange at the eighth drilling mud inlet 38205 and/or the eighth drilling mud outlet 38210.

In an embodiment, the second drilling mud manifold 38215 may have an integral flange at the second, first drilling mud outlet 38220, the second, second drilling mud outlet 38225, the second, third drilling mud outlet 38230, and the second, fourth drilling mud outlet 38235.

In an embodiment, the eighth drilling mud outlet 38210 of the eighth gate valve 38200 may be fluidly connected to the second, fourth drilling mud inlet 38235 of the second drilling mud manifold 38215. In an embodiment, the eighth drilling mud outlet 38210 of the eighth gate valve 38200 may be sealed to the second, fourth drilling mud inlet 38235 of the second drilling mud manifold 38215 via a gasket or an O-ring. Any suitable gasket or O-ring may be used. For example, suitable O-rings include, but are not limited to, 300 Series O-rings. Gaskets and O-rings are well known in the art.

Second Alternative Optional Flow Loop Configuration

In an embodiment, four or more drilling mud screen systems may be used in an optional flow loop configuration to create a redundancy, reduce number of gate valves, and/or to increase through put.

FIG. 39A illustrates an upper, left perspective view of a drilling mud screen system in a flow loop configuration 3900, showing eight drilling mud screen systems; FIG. 39B illustrates a left side view of the flow loop configuration 3900 of FIG. 39A, showing a drilling mud inlet; FIG. 39C illustrates a right side view of the flow loop configuration 3900 of FIG. 39A, showing a drilling mud outlet; and FIG. 39D illustrates a back view of the flow loop configuration 3900 of FIG. 39A.

FIG. 40A illustrates an upper, right perspective view of a drilling mud screen system in a flow loop configuration 4000; FIG. 40B illustrates a left side view of the flow loop configuration 4000 of FIG. 40A, showing a drilling mud inlet; FIG. 40C illustrates a right side view of the flow loop

configuration 4000 of FIG. 40A, showing a drilling mud outlet; and FIG. 40D illustrates a top view of the flow loop configuration 4000 of FIG. 40A.

As shown in FIGS. 39A-40D, the flow loop configuration 3900, 4000 comprises a first drilling mud manifold 3905, 4005 having a first drilling mud inlet 3910, 4010 and a first drilling mud outlet 3915, 4015, a first spool 3920, 4020 having a first drilling mud inlet 3925, 4025 and a first drilling mud outlet 3930, 4030, a second drilling mud manifold 3935, 4035 having a second drilling mud inlet 3940, 4040, a second drilling mud outlet 3945, 4045, a second spool 3950, 4050 having a second drilling mud inlet 3955, 4055 and a second drilling mud outlet 3960, 4060, a third drilling mud manifold 3965, 4065 having a third drilling mud inlet 3970, 4070, a third, first drilling mud outlet 3975a, 4075a and a third, second drilling mud outlet 3975b, 4075b, a first gate valve 3980, 4080 having a first drilling mud inlet 3985, 4085 and a first drilling mud outlet 3990, 4090, a fourth drilling mud manifold 3995, 4095 having a fourth drilling mud inlet 39100, 40100, a fourth, first drilling mud outlet 39105a, 40105a, a fourth, second drilling mud outlet 39105b, 40105b, a fourth, third drilling mud outlet 39105c, 40105c and a fourth, fourth drilling mud outlet 39105d, 40105d, a third spool 39110, 40110 having a third drilling mud inlet 39115, 40115 and a third drilling mud outlet 39120, 40120, a fifth drilling mud manifold 39125, 40125 having a fifth drilling mud inlet 39130, 40130 and a fifth drilling mud outlet 39135, 40135, a second gate valve 39140, 40140 having a second drilling mud inlet 39145, 40145 and a second drilling mud outlet 39150, 40150, a sixth drilling mud manifold 39155, 40155 having a sixth drilling mud inlet 39160, 40160, a sixth, first drilling mud outlet 39165a, 40165a, a sixth, second drilling mud outlet 39165b, 40165b, a sixth, third drilling mud outlet 39165c, 40165c, a sixth, fourth drilling mud outlet 39165d, 40165d, a first drilling mud screen system 400, 600, 1400, 2100, 2300, 39170, 40170 having a first drilling mud inlet 420, 620a, 1420, 2120a, 2320a, 39175, 40175 and a first drilling mud outlet 425, 625b, 1425, 2120b, 39180, 40180, a second drilling mud screen system 400, 600, 1400, 2100, 2300, 39185, 40185 having a second drilling mud inlet 420, 620a, 1420, 2120a, 2320a, 39190, 40190, a second drilling mud outlet 425, 625b, 1425, 2125b, 2325b, 39195, 40195, a third drilling mud screen system 400, 600, 1400, 2100, 2300, 39200, 40200 having a third drilling mud inlet 420, 620a, 1420, 2120a, 2320a, 39205, 40205 and a third drilling mud outlet 425, 625b, 1425, 2120b, 39210, 40210, a fourth drilling mud screen system 400, 600, 1400, 2100, 2300, 39215, 40215 having a fourth drilling mud inlet 420, 620a, 1420, 2120a, 2320a, 39220, 40220 and a fourth drilling mud outlet 425, 625b, 1425, 2120b, 39225, 40225, a fifth drilling mud screen system 400, 600, 1400, 2100, 2300, 39230, 40230 having a fifth drilling mud inlet 420, 620a, 1420, 2120a, 2320a, 39235, 40235 and a fifth drilling mud outlet 425, 625b, 1425, 2120b, 39240, 40240, a sixth drilling mud screen system 400, 600, 1400, 2100, 2300, 39245, 40245 having a sixth drilling mud inlet 420, 620a, 1420, 2120a, 2320a, 39250, 40250 and a fifth drilling mud outlet 425, 625b, 1425, 2120b, 39255, 40255, a seventh drilling mud screen system 400, 600, 1400, 2100, 2300, 39260, 40260 having a seventh drilling mud inlet 420, 620a, 1420, 2120a, 2320a, 39265, 40265 and a seventh drilling mud outlet 425, 625b, 1425, 2120b, 39270, 40270, an eighth drilling mud screen system 400, 600, 1400, 2100, 2300, 39275, 40275 having a drilling mud inlet 420, 620a, 1420, 2120a, 2320a, 39280, 40280 and a seventh drilling mud outlet 425, 625b, 1425, 2120b, 39285, 40285, third gate valve 39320, 40320

having a third drilling mud inlet **39325, 40325** and a third drilling mud outlet **39330, 40330**, a fourth gate valve **39335, 40335** having a fourth drilling mud inlet **39340, 40340** and a fourth drilling mud outlet **39345, 40345**, a ninth drilling mud manifold **39350, 40350** having a ninth, first drilling mud inlet **39355a, 40355a**, a ninth, second drilling mud inlet **39355b, 40355b** and a ninth drilling mud outlet **39360, 40360**, a fourth spool **39365, 40365** having a fourth drilling mud inlet **39370, 40370** and a fourth drilling mud outlet **39375, 40375**, a tenth drilling mud manifold **39380, 40380** having a tenth drilling mud inlet **39385, 40385** and a tenth drilling mud outlet **39390, 40390**, a fifth spool **39395, 40395** having a fifth drilling mud inlet **39400, 40400** and a fifth drilling mud outlet **39405, 40405**, and an eleventh drilling mud manifold **39410, 40410** having an eleventh drilling mud inlet **39415, 40415** and an eleventh drilling mud outlet **39420, 40420**.

In an embodiment, the drilling mud inlet **3910, 4010** may be fluidly connected to, for example, an outlet of a drilling mud pump via a connection; and the drilling mud outlet **39420, 40420** may be fluidly connected to an inlet of a vibrator hose via a connection. Any suitable connection may be used for the drilling mud inlet **3910, 4010** and drilling mud outlet **39420, 40420**. For example, suitable connections include, but are not limited to, pipe fittings and welds. Connections are well known in the art. In an embodiment, the drilling mud inlet **3910, 4010** may be fluidly connected to, for example, an outlet of a drilling mud pump via a weld; and the drilling mud outlet **39420, 4420** may be fluidly connected to an inlet of a vibrator hose via a weld.

In an embodiment, the flow loop configuration **3900, 4000** comprises a first stub connection from, for example, an outlet of a drilling mud pump to a drilling mud inlet **3910, 4010** of a first drilling mud manifold **3905, 4005**.

In an embodiment, the flow loop configuration **3900, 4000** comprises a second stub connection from, for example, a drilling mud outlet **3942, 40420** of an eleventh drilling mud manifold **39410, 40410** to an inlet of a vibrator hose.

In an embodiment, the first drilling mud outlet **3915, 4015** of the first drilling mud manifold **3905, 4005** and the first spool **3920, 4020** may be fluidly connected by a connection. Any suitable connection may be used for the first drilling mud outlet **3915, 4015** of the first drilling mud manifold **3905, 4005** and the first spool **3920, 4020**. For example, suitable connections include, but are not limited to, flanges and pipe fittings. Connections are well known in the art.

In an embodiment, the first drilling mud manifold **3905, 4005** may have an integral flange at the first drilling mud outlet **3915, 4015**.

In an embodiment, the first spool **3920, 4020** may have an integral flange at the first drilling mud inlet **3925, 4025** and/or the first drilling mud outlet **3930, 4030**.

In an embodiment, the first drilling mud outlet **3930, 4030** of the first spool **3920, 4020** and the second drilling mud manifold **3935, 4035** may be fluidly connected by a connection. Any suitable connection may be used for the first drilling mud outlet **3930, 4030** of the first spool **3920, 4020** and the second drilling mud manifold **3935, 4035**. For example, suitable connections include, but are not limited to, flanges and pipe fittings. Connections are well known in the art.

In an embodiment, the first spool **3920, 4020** may have an integral flange at the first drilling mud inlet **3925, 4025** and/or the first drilling mud outlet **3930, 4030**.

In an embodiment, the second drilling mud manifold **3935, 4035** may have an integral flange at the second drilling mud inlet **3940, 4040** and/or the second drilling mud outlet **3945, 4045**.

5 In an embodiment, the second drilling mud outlet **3945, 4045** of the second drilling mud manifold **3935, 4035** and the second spool **3950, 4050** may be fluidly connected by a connection. Any suitable connection may be used for the second drilling mud outlet **3945, 4045** of the second drilling mud manifold **3935, 4035** and the second spool **3950, 4050**. For example, suitable connections include, but are not limited to, flanges and pipe fittings. Connections are well known in the art.

15 In an embodiment, the second drilling mud manifold **3935, 4035** may have an integral flange at the second drilling mud inlet **3940, 4040** and/or the second drilling mud outlet **3945, 4045**.

20 In an embodiment, the second spool **3950, 4050** may have an integral flange at the second drilling mud inlet **3955, 4055** and/or the second drilling mud outlet **3960, 4060**.

25 In an embodiment, the second drilling mud outlet **3960, 4060** of the second spool **3950, 4050** and the third drilling mud manifold **3965, 4065** may be fluidly connected by a connection. Any suitable connection may be used for the second drilling mud outlet **3960, 4060** of the second spool **3950, 4050** and the third drilling mud manifold **3965, 4065**. For example, suitable connections include, but are not limited to, flanges and pipe fittings. Connections are well known in the art.

30 In an embodiment, the second spool **3950, 4050** may have an integral flange at the second drilling mud inlet **3955, 4055** and/or the second drilling mud outlet **3960, 4060**.

35 In an embodiment, the third drilling mud manifold **3965, 4065** may have an integral flange at the third drilling mud inlet **3970, 4070**, the third, first drilling mud outlet **3975a, 4075a**, **4075a** and/or the third, second drilling mud outlet **3975b, 4075b**.

40 In an embodiment, the third, first drilling mud outlet **3975a, 4075a** of the third drilling mud manifold **3965, 4065** and the first gate valve **3980, 4080** may be fluidly connected via a connection. Any suitable connection may be used for the third, first drilling mud outlet **3975a, 4075a** of the third drilling mud manifold **3965, 4065** and the first gate valve **3980, 4080**. For example, suitable connections include, but are not limited to, flanges and pipe fittings. Connections are well known in the art.

45 In an embodiment, the third drilling mud manifold **3965, 4065** may have an integral flange at the third drilling mud inlet **3970, 4070**, the third, first drilling mud outlet **3975a, 4075a** and/or the third, second drilling mud outlet **3975b, 4075b**.

50 In an embodiment, the first gate valve **3980, 4080** may have an integral flange at the first drilling mud inlet **3985, 4085** and/or the first drilling mud outlet **3990, 4090**.

55 In an embodiment, the first drilling mud outlet **3990, 4090** of the first gate valve **3980, 4080** and the fourth drilling mud manifold **3995, 4095** may be fluidly connected via a connection. Any suitable connection may be used for the first drilling mud outlet **3990, 4090** of the first gate valve **3980, 4080** and the fourth drilling mud manifold **3995, 4095**. For example, suitable connections include, but are not limited to, flanges and pipe fittings. Connections are well known in the art.

60 In an embodiment, the first gate valve **3980, 4080** may have an integral flange at the first drilling mud inlet **3985, 4085** and/or the first drilling mud outlet **3990, 4090**.

In an embodiment, the fourth drilling mud manifold **3995, 4095** may have an integral flange at the fourth drilling mud inlet **39100, 40100**, the fourth, first drilling mud outlet **39105a, 40105a**, the fourth, second drilling mud outlet **39405b, 40405b**, the fourth, third drilling mud outlet **39405c, 40405c**, and/or the fourth, fourth drilling mud outlet **39405d, 40405d**.

In an embodiment, the third, second drilling mud outlet **3975b, 4075b** of the third drilling mud manifold **3965, 4065** and the third spool **39110, 40110** may be fluidly connected by a connection. Any suitable connection may be used for the third, second drilling mud outlet **3975b, 4075b** of the third drilling mud manifold **3965, 4065** and the third spool **39110, 40110**. For example, suitable connections include, but are not limited to, flanges and pipe fittings. Connections are well known in the art.

In an embodiment, the third drilling mud manifold **3965, 4065** may have an integral flange at the third drilling mud inlet **3970, 4070**, the third, first drilling mud outlet **3975a, 4075a** and/or the third, second drilling mud outlet **3975b, 4075b**.

In an embodiment, the third spool **39110, 40110** may have an integral flange at the third drilling mud inlet **39115, 40115** and/or the third drilling mud outlet **39120, 40120**.

In an embodiment, the third drilling mud outlet **39120, 40120** of the third spool **39110, 40110** and a fifth drilling mud manifold **39125, 40125** may be fluidly connected via a connection. Any suitable connection may be used for the third drilling mud outlet **39120, 40120** of the third spool **39110, 40110** and the fifth drilling mud manifold **39125, 40125**. For example, suitable connections include, but are not limited to, flanges and pipe fittings. Connections are well known in the art.

In an embodiment, the third spool **39110, 40110** may have an integral flange at the third drilling mud inlet **39115, 40115** and/or the third drilling mud outlet **39120, 40120**.

In an embodiment, the fifth drilling mud manifold **39125, 40125** may have an integral flange at the fifth drilling mud inlet **39130, 40130** and/or the fifth drilling mud outlet **39135, 40135**.

In an embodiment, the fifth drilling mud outlet **39135, 40135** of the fifth drilling mud manifold **39125, 40125** and the second gate valve **39140, 40140** may be fluidly connected via a connection. Any suitable connection may be used for the fifth drilling mud outlet **39135, 40135** of the fifth drilling mud manifold **39125, 40125** and the second gate valve **39140, 40140**. For example, suitable connections include, but are not limited to, flanges and pipe fittings. Connections are well known in the art.

In an embodiment, the fifth drilling mud manifold **39125, 40125** may have an integral flange at the fifth drilling mud inlet **39130, 40130** and/or the fifth drilling mud outlet **39135, 40135**.

In an embodiment, the second gate valve **39140, 40140** may have an integral flange at the second drilling mud inlet **39145, 40145** and/or the second drilling mud outlet **39150, 40150**.

In an embodiment, the second drilling mud outlet **39150, 40150** of the second gate valve **39140, 40140** and the sixth drilling mud manifold **39155, 40155** may be fluidly connected via a connector. Any suitable connector may be used for the second drilling mud outlet **39150, 40150** of the second gate valve **39140, 40140** and the sixth drilling mud manifold **39155, 40155**. For example, suitable connections include, but are not limited to, flanges and pipe fittings. Connections are well known in the art.

In an embodiment, the second gate valve **39140, 40140** may have an integral flange at the second drilling mud inlet **39145, 40145** and/or the second drilling mud outlet **39150, 40150**.

5 In an embodiment, the sixth drilling mud manifold **39155, 40155** may have an integral flange at the sixth drilling mud inlet **39160, 40160**, the sixth, first drilling mud outlet **39165a, 40165a**, the sixth, second drilling mud outlet **39165b, 40165b**, the sixth, third drilling mud outlet **39165c, 40165c** and/or the sixth, fourth drilling mud outlet **39165d, 40165d**.

In an embodiment, the fourth, first drilling mud outlet **39105a, 40105a** of the fourth drilling mud manifold **3995, 4095** and the first drilling mud inlet **420, 620a, 1420, 2120a, 2320a, 39175, 40175** of the first drilling mud screen system **400, 600, 1400, 2100, 2300, 39170, 40170** may be fluidly connected by a connection. Any suitable connection may be used for the fourth, first drilling mud outlet **39105a, 40105a** of the fourth drilling mud manifold **3995, 4095** and the first drilling mud inlet **420, 620a, 1420, 2120a, 2320a, 39175, 40175** of the first drilling mud screen system **400, 600, 1400, 2100, 2300, 39170, 40170**. For example, suitable connections include, but are not limited to, flanges and pipe fittings. Connections are well known in the art.

In an embodiment, the fourth drilling mud manifold **3995, 4095** may have an integral flange at the fourth drilling mud inlet **39100, 40100**, the fourth, first drilling mud outlet **39105a, 40105a**, the fourth, second drilling mud outlet **39105b, 40105b**, the fourth, third drilling mud outlet **39105c, 40105c** and/or the fourth, fourth drilling mud outlet **39105d, 40105d**.

In an embodiment, the flow loop configuration **3900, 4000** comprises a first cross-over connection **3105, 39425, 40425** from a fourth drilling mud manifold **3995, 4095** to a first drilling mud screen system **400, 600, 1400, 2100, 2300, 39170, 40170**.

In an embodiment, the first cross-over connection **3105, 39425, 40425** may have an integral flange at a first drilling mud inlet and/or a first drilling mud outlet.

In an embodiment, the fourth, second drilling mud outlet **39105b, 40105b** of the fourth drilling mud manifold **3995, 4095** and the second drilling mud inlet **420, 620a, 1420, 2120a, 2320a, 39190, 40190** of the second drilling mud screen system **400, 600, 1400, 2100, 2300, 39185, 40185** may be fluidly connected by a connection. Any suitable connection may be used for the fourth, second drilling mud outlet **39105b, 40105b** of the fourth drilling mud manifold **3995, 4095** and the second drilling mud inlet **420, 620a, 1420, 2120a, 2320a, 39190, 40190** of the second drilling mud screen system **400, 600, 1400, 2100, 2300, 39185, 40185**. For example, suitable connections include, but are not limited to, flanges and pipe fittings. Connections are well known in the art.

In an embodiment, the fourth drilling mud manifold **3995, 4095** may have an integral flange at the fourth drilling mud inlet **39100, 40100**, the fourth, first drilling mud outlet **39105a, 40105a**, the fourth, second drilling mud outlet **39105b, 40105b**, the fourth, third drilling mud outlet **39105c, 40105c** and/or the fourth, fourth drilling mud outlet **39105d, 40105d**.

In an embodiment, the flow loop configuration **3900, 4000** comprises a second cross-over connection **3105, 39430, 40430** from a fourth drilling mud manifold **3995, 4095** to a second drilling mud screen system **400, 600, 1400, 2100, 2300, 39185, 40185**.

In an embodiment, the second cross-over connection **3105, 39430, 40430** may have an integral flange at a second drilling mud inlet.

In an embodiment, the fourth, third drilling mud outlet **39105c, 40105c** of the fourth drilling mud manifold **3995, 4095** and the third drilling mud inlet **420, 620a, 1420, 2120a, 2320a, 39205, 40205** of the third drilling mud screen system **400, 600, 1400, 2100, 2300, 39200, 40200** may be fluidly connected by a connection. Any suitable connection may be used for the fourth, third drilling mud outlet **39105c, 40105c** of the fourth drilling mud manifold **3995, 4095** and the third drilling mud inlet **420, 620a, 1420, 2120a, 2320a, 39205, 40205** of the third drilling mud screen system **400, 600, 1400, 2100, 2300, 39200, 40200**. For example, suitable connections include, but are not limited to, flanges and pipe fittings. Connections are well known in the art.

In an embodiment, the fourth drilling mud manifold **3995, 4095** may have an integral flange at the fourth drilling mud inlet **39100, 40100**, the fourth, first drilling mud outlet **39105a, 40105a**, the fourth, second drilling mud outlet **39105b, 40105b**, the fourth, third drilling mud outlet **39105c, 40105c** and/or the fourth, fourth drilling mud outlet **39105d, 40105d**.

In an embodiment, the flow loop configuration **3900, 4000** comprises a third cross-over connection **3105, 39435, 40435** from a fourth drilling mud manifold **3995, 4095** to a third drilling mud screen system **400, 600, 1400, 2100, 2300, 39200, 40200**.

In an embodiment, the third cross-over connection **3105, 39435, 40435** may have an integral flange at a third drilling mud inlet and/or a third drilling mud outlet.

In an embodiment, the fourth, fourth drilling mud outlet **39105d, 40105d** of the fourth drilling mud manifold **3995, 4095** and the fourth drilling mud inlet **420, 620a, 1420, 2120a, 2320a, 39220, 40220** of the fourth drilling mud screen system **400, 600, 1400, 2100, 2300, 39215, 40215** may be fluidly connected by a connection. Any suitable connection may be used for the fourth, fourth drilling mud outlet **39105d, 40105d** of the fourth drilling mud manifold **3995, 4095** and the fourth drilling mud inlet **420, 620a, 1420, 2120a, 2320a, 39220, 40220** of the fourth drilling mud screen system **400, 600, 1400, 2100, 2300, 39215, 40215**. For example, suitable connections include, but are not limited to, flanges and pipe fittings. Connections are well known in the art.

In an embodiment, the fourth drilling mud manifold **3995, 4095** may have an integral flange at the fourth drilling mud inlet **39100, 40100**, the fourth, first drilling mud outlet **39105a, 40105a**, the fourth, second drilling mud outlet **39105b, 40105b**, the fourth, third drilling mud outlet **39105c, 40105c** and/or the fourth, fourth drilling mud outlet **39105d, 40105d**.

In an embodiment, the flow loop configuration **3900, 4000** comprises a fourth cross-over connection **3105, 39440, 40440** from a fourth drilling mud manifold **3995, 4095** to a fourth drilling mud screen system **400, 600, 1400, 2100, 2300, 39215, 40215**.

In an embodiment, the fourth cross-over connection **3105, 39440, 40440** may have an integral flange at a fourth drilling mud inlet and/or a fourth drilling mud outlet.

In an embodiment, the sixth, first drilling mud outlet **39165a, 40165a** of the sixth drilling mud manifold **39155, 40155** and the fifth drilling mud inlet **420, 620a, 1420, 2120a, 2320a, 39235, 40235** of the fifth drilling mud screen system **400, 600, 1400, 2100, 2300, 39230, 40230** may be fluidly connected by a connection. Any suitable connection may be used for the sixth, first drilling mud outlet **39165a**,

40165a of the sixth drilling mud manifold **39155, 40155** and the fifth drilling mud inlet **420, 620a, 1420, 2120a, 2320a, 39235, 40235** of the fifth drilling mud screen system **400, 600, 1400, 2100, 2300, 39230, 40230**. For example, suitable connections include, but are not limited to, flanges and pipe fittings. Connections are well known in the art.

In an embodiment, the sixth drilling mud manifold **39155, 40155** may have an integral flange at the sixth drilling mud inlet **39160, 40160**, the sixth, first drilling mud outlet **39165a, 40165a**, the sixth, second drilling mud outlet **39165b, 40165b**, the sixth, third drilling mud outlet **39165c, 40165c** and/or the sixth, fourth drilling mud outlet **39165d, 40165d**.

In an embodiment, the flow loop configuration **3900, 4000** comprises a fifth cross-over connection **3105, 39445, 40445** from a sixth drilling mud manifold **39155, 40155** to a fifth drilling mud screen system **400, 600, 1400, 2100, 2300, 39230, 40230**.

In an embodiment, the fifth cross-over connection **3105, 39445, 40445** may have an integral flange at a fifth drilling mud inlet and/or a fifth drilling mud outlet.

In an embodiment, the sixth, second drilling mud outlet **39165b, 40165b** of the sixth drilling mud manifold **39155, 40155** and the sixth drilling mud inlet **420, 620a, 1420, 2120a, 2320a, 39250, 40250** of the sixth drilling mud screen system **400, 600, 1400, 2100, 2300, 39245, 40245** may be fluidly connected by a connection. Any suitable connection may be used for the sixth, second drilling mud outlet **39165b, 40165b** of the sixth drilling mud manifold **39155, 40155** and the sixth drilling mud inlet **420, 620a, 1420, 2120a, 2320a, 39250, 40250** of the sixth drilling mud screen system **400, 600, 1400, 2100, 2300, 39245, 40245**. For example, suitable connections include, but are not limited to, flanges and pipe fittings. Connections are well known in the art.

In an embodiment, the sixth drilling mud manifold **39155, 40155** may have an integral flange at the sixth drilling mud inlet **39160, 40160**, the sixth, first drilling mud outlet **39165a, 40165a**, the sixth, second drilling mud outlet **39165b, 40165b**, the sixth, third drilling mud outlet **39165c, 40165c** and/or the sixth, fourth drilling mud outlet **39165d, 40165d**.

In an embodiment, the flow loop configuration **3900, 4000** comprises a sixth cross-over connection **3105, 39450, 40450** from a sixth drilling mud manifold **39155, 40155** to a sixth drilling mud screen system **400, 600, 1400, 2100, 2300, 39245, 40245**.

In an embodiment, the sixth cross-over connection **3105, 39450, 40450** may have an integral flange at a sixth drilling mud inlet and/or a sixth drilling mud outlet.

In an embodiment, the sixth, third drilling mud outlet **39165c, 40165c** of the sixth drilling mud manifold **39155, 40155** and the seventh drilling mud inlet **420, 620a, 1420, 2120a, 2320a, 39265, 40265** of the seventh drilling mud screen system **400, 600, 1400, 2100, 2300, 39260, 40260** may be fluidly connected by a connection. Any suitable connection may be used for the sixth, third drilling mud outlet **39165c, 40165c** of the sixth drilling mud manifold **39155, 40155** and the seventh drilling mud inlet **420, 620a, 1420, 2120a, 2320a, 39265, 40265** of the seventh drilling mud screen system **400, 600, 1400, 2100, 2300, 39260, 40260**. For example, suitable connections include, but are not limited to, flanges and pipe fittings. Connections are well known in the art.

In an embodiment, the sixth drilling mud manifold **39155, 40155** may have an integral flange at the sixth drilling mud inlet **39160, 40160**, the sixth, first drilling mud outlet

39165a, 40165a, the sixth, second drilling mud outlet 39165b, 40165b, the sixth, third drilling mud outlet 39165c, 40165c and/or the sixth, fourth drilling mud outlet 39165d, 40165d.

In an embodiment, the flow loop configuration 3900, 4000 comprises a seventh cross-over connection 3105, 39455, 40455 from a sixth drilling mud manifold 39155, 40155 to a seventh drilling mud screen system 400, 600, 1400, 2100, 2300, 39260, 40260.

In an embodiment, the seventh cross-over connection 3105, 39455, 40455 may have an integral flange at a seventh drilling mud inlet and/or a seventh drilling mud outlet.

In an embodiment, the sixth, fourth drilling mud outlet 39165d, 40165d of the sixth drilling mud manifold 39155, 40155 and the eighth drilling mud inlet 420, 620a, 1420, 2120a, 2320a, 39280, 40280 of the eighth drilling mud screen system 400, 600, 1400, 2100, 2300, 39275, 40275 may be fluidly connected by a connection. Any suitable connection may be used for the sixth, fourth drilling mud outlet 39165d, 40165d of the sixth drilling mud manifold 39155, 40155 and the eighth drilling mud inlet 420, 620a, 1420, 2120a, 2320a, 39280, 40280 of the eighth drilling mud screen system 400, 600, 1400, 2100, 2300, 39275, 40275. For example, suitable connections include, but are not limited to, flanges and pipe fittings. Connections are well known in the art.

In an embodiment, the sixth drilling mud manifold 39155, 40155 may have an integral flange at the sixth drilling mud inlet 39160, 40160, the sixth, first drilling mud outlet 39165a, 40165a, the sixth, second drilling mud outlet 39165b, 40165b, the sixth, third drilling mud outlet 39165c, 40165c and/or the sixth, fourth drilling mud outlet 39165d, 40165d.

In an embodiment, the flow loop configuration 3900, 4000 comprises a eighth cross-over connection 3105, 39460, 40460 from a sixth drilling mud manifold 39155, 40155 to an eighth drilling mud screen system 400, 600, 1400, 2100, 2300, 39275, 40275.

In an embodiment, the eighth cross-over connection 3105, 39460, 40460 may have an integral flange at an eighth drilling mud inlet and/or an eighth drilling mud outlet.

In an embodiment, the first drilling mud outlet 425, 625b, 1425, 2125b, 2325b, 39180, 40180 of the first drilling mud screen system 400, 600, 1400, 2100, 2300, 39170, 40170 and the seventh, first drilling mud inlet 39295a, 40295a of the seventh drilling mud manifold 39290, 40290 may be fluidly connected by a connection. Any suitable connection may be used for the first drilling mud outlet 425, 625b, 1425, 2125b, 2325b, 39180, 40180 of the first drilling mud screen system 400, 600, 1400, 2100, 2300, 39170, 40170 and the seventh, first drilling mud inlet 39295a, 40295a of the seventh drilling mud manifold 39290, 40290. For example, suitable connections include, but are not limited to, flanges and pipe fittings. Connections are well known in the art.

In an embodiment, the flow loop configuration 3900, 4000 comprises a ninth cross-over connection 3105, 39465, 40465 from a first drilling mud screen system 400, 600, 1400, 2100, 2300, 39170, 40170 to a seventh drilling mud manifold 39290, 40290.

In an embodiment, the ninth cross-over connection 3105, 39465, 40465 may have an integral flange at a ninth drilling mud outlet.

In an embodiment, the seventh drilling mud manifold 39290, 40290 may have an integral flange at the seventh, first drilling mud inlet 39295a, 40295a, the seventh, second drilling mud inlet 39295b, 40295b, the seventh, third drilling

mud inlet 39295c, 40295c, the seventh, fourth drilling mud inlet 39295d, 40295d and/or the seventh drilling mud outlet 39300, 40300.

In an embodiment, the second drilling mud outlet 425, 625b, 1425, 2125b, 2325b, 39195, 40195 of the second drilling mud screen system 400, 600, 1400, 2100, 2300, 39185, 40185 and the seventh, second drilling mud inlet 39295b, 40295b of the seventh drilling mud manifold 39290, 40290 may be fluidly connected by a connection.

10 Any suitable connection may be used for the second drilling mud outlet 425, 625b, 1425, 2125b, 2325b, 39195, 40195 of the second drilling mud screen system 400, 600, 1300, 2100, 2300, 39185, 40185 and the seventh, second drilling mud inlet 39295b, 40295b of the seventh drilling mud manifold 39290, 40290. For example, suitable connections include, but are not limited to, flanges and pipe fittings. Connections are well known in the art.

In an embodiment, the flow loop configuration 3900, 4000 comprises a tenth cross-over connection 3105, 39470, 40470 20 from a second drilling mud screen system 400, 600, 1400, 2100, 2300, 39185, 40185 to a seventh drilling mud manifold 39290, 40290.

In an embodiment, the tenth cross-over connection 3105, 39470, 40470 may have an integral flange at a tenth drilling mud outlet.

25 In an embodiment, the seventh drilling mud manifold 39290, 40290 may have an integral flange at the seventh, first drilling mud inlet 39295a, 40295a, the seventh, second drilling mud inlet 39295b, 40295b, the seventh, third drilling mud inlet 39295c, 40295c, the seventh, fourth drilling mud inlet 39295d, 40295d and/or the seventh drilling mud outlet 39300, 40300.

30 In an embodiment, the third drilling mud outlet 425, 625b, 1425, 2125b, 2325b, 39205, 40205 of the third drilling mud screen system 400, 600, 1400, 2100, 2300, 39200, 40200 and the seventh, third drilling mud inlet 39295c, 40295c of the seventh drilling mud manifold 39290, 40290 may be fluidly connected by a connection. Any suitable connection may be used for the third drilling mud outlet 425, 625b, 1425, 2125b, 2325b, 39205, 40205 of the third drilling mud screen system 400, 600, 1300, 2100, 2300, 39200, 40200 and the seventh, third drilling mud inlet 39295c, 40295c of the seventh drilling mud manifold 39290, 40290. For example, suitable connections include, but are not limited to, flanges and pipe fittings. Connections are well known in the art.

35 In an embodiment, the flow loop configuration 3900, 4000 comprises an eleventh cross-over connection 3105, 39475, 40475 from a third drilling mud screen system 400, 600, 1400, 2100, 2300, 39200, 40200 to a seventh drilling mud manifold 39290, 40290.

40 In an embodiment, the eleventh cross-over connection 3105, 39475, 40475 may have an integral flange at an eleventh drilling mud outlet.

45 In an embodiment, the seventh drilling mud manifold 39290, 40290 may have an integral flange at the seventh, first drilling mud inlet 39295a, 40295a, the seventh, second drilling mud inlet 39295b, 40295b, the seventh, third drilling mud inlet 39295c, 40295c, the seventh, fourth drilling mud inlet 39295d, 40295d and/or the seventh drilling mud outlet 39300, 40300.

50 In an embodiment, the fourth drilling mud outlet 425, 625b, 1425, 2125b, 2325b, 39225, 40225 of the fourth drilling mud screen system 400, 600, 1400, 2100, 2300, 39215, 40215 and the seventh, fourth drilling mud inlet 39295d, 40295d of the seventh drilling mud manifold 39290, 40290 may be fluidly connected by a connection.

Any suitable connection may be used for the fourth drilling mud outlet **425, 625b, 1425, 2125b, 2325b, 39225, 40225** of the fourth drilling mud screen system **400, 600, 1300, 2100, 2300, 39215, 40215** and the seventh, fourth drilling mud inlet **39295d, 40295d** of the seventh drilling mud manifold **39290, 40290**. For example, suitable connections include, but are not limited to, flanges and pipe fittings. Connections are well known in the art.

In an embodiment, the flow loop configuration **3900, 4000** comprises a twelfth cross-over connection **3105, 39480, 40480** from a fourth drilling mud screen system **400, 600, 1400, 2100, 2300, 39215, 40215** to a seventh drilling mud manifold **39290, 40290**.

In an embodiment, the twelfth cross-over connection **3105, 39480, 40480** may have an integral flange at a twelfth drilling mud outlet.

In an embodiment, the seventh drilling mud manifold **39290, 40290** may have an integral flange at the seventh, first drilling mud inlet **39295a, 40295a**, the seventh, second drilling mud inlet **39295b, 40295b**, the seventh, third drilling mud inlet **39295c, 40295c**, the seventh, fourth drilling mud inlet **39295d, 40295d** and/or the seventh drilling mud outlet **39300, 40300**.

In an embodiment, the fifth drilling mud outlet **425, 625b, 1425, 2125b, 2325b, 39240, 40240** of the fifth drilling mud screen system **400, 600, 1400, 2100, 2300, 39230, 40230** and the eighth, first drilling mud inlet **39310a, 40310a** of the eighth drilling mud manifold **39305, 40305** may be fluidly connected by a connection. Any suitable connection may be used for the fifth drilling mud outlet **425, 625b, 1425, 2125b, 2325b, 39240, 40240** of the fifth drilling mud screen system **400, 600, 1300, 2100, 2300, 39230, 40230** and the eighth, first drilling mud inlet **39310a, 40310a** of the eighth drilling mud manifold **39305, 40305**. For example, suitable connections include, but are not limited to, flanges and pipe fittings. Connections are well known in the art.

In an embodiment, the flow loop configuration **3900, 4000** comprises a thirteenth cross-over connection **3105, 39485, 40485** from a fifth drilling mud screen system **400, 600, 1400, 2100, 2300, 39230, 40230** to an eighth drilling mud manifold **39305, 40305**.

In an embodiment, the thirteenth cross-over connection **3105, 39485, 40485** may have an integral flange at a thirteenth drilling mud outlet.

In an embodiment, the eighth drilling mud manifold **39305, 40305** may have an integral flange at the eighth, first drilling mud inlet **39310a, 40310a**, the eighth, second drilling mud inlet **39310b, 40310b**, the eighth, third drilling mud inlet **39310c, 40310c**, the eighth, fourth drilling mud inlet **39310d, 40310d** and/or the eighth drilling mud outlet **39315, 40315**.

In an embodiment, the sixth drilling mud outlet **425, 625b, 1425, 2125b, 2325b, 39255, 40255** of the sixth drilling mud screen system **400, 600, 1400, 2100, 2300, 39245, 40245** and the eighth, second drilling mud inlet **39310b, 40310b** of the eighth drilling mud manifold **39305, 40305** may be fluidly connected by a connection. Any suitable connection may be used for the sixth drilling mud outlet **425, 625b, 1425, 2125b, 2325b, 39255, 40255** of the sixth drilling mud screen system **400, 600, 1300, 2100, 2300, 39245, 40245** and the eighth, second drilling mud inlet **39310b, 40310b** of the eighth drilling mud manifold **39305, 40305**. For example, suitable connections include, but are not limited to, flanges and pipe fittings. Connections are well known in the art.

In an embodiment, the flow loop configuration **3900, 4000** comprises a fourteenth cross-over connection **3105, 39490,**

40490 from a sixth drilling mud screen system **400, 600, 1400, 2100, 2300, 39245, 40245** to an eighth drilling mud manifold **39305, 40305**.

In an embodiment, the fourteenth cross-over connection **3105, 39490, 40490** may have an integral flange at a fourteenth drilling mud outlet.

In an embodiment, the eighth drilling mud manifold **39305, 40305** may have an integral flange at the eighth, first drilling mud inlet **39310a, 40310a**, the eighth, second drilling mud inlet **39310b, 40310b**, the eighth, third drilling mud inlet **39310c, 40310c**, the eighth, fourth drilling mud inlet **39310d, 40310d** and/or the eighth drilling mud outlet **39315, 40315**.

In an embodiment, the seventh drilling mud outlet **425, 625b, 1425, 2125b, 2325b, 39270, 40270** of the seventh drilling mud screen system **400, 600, 1400, 2100, 2300, 39260, 40260** and the eighth, third drilling mud inlet **39310c, 40310c** of the eighth drilling mud manifold **39305, 40305** may be fluidly connected by a connection. Any suitable connection may be used for the seventh drilling mud outlet **425, 625b, 1425, 2125b, 2325b, 39270, 40270** of the seventh drilling mud screen system **400, 600, 1300, 2100, 2300, 39260, 40260** and the eighth, third drilling mud inlet **39310c, 40310c** of the eighth drilling mud manifold **39305, 40305**. For example, suitable connections include, but are not limited to, flanges and pipe fittings. Connections are well known in the art.

In an embodiment, the flow loop configuration **3900, 4000** comprises a fifteenth cross-over connection **3105, 39495, 40495** from a seventh drilling mud screen system **400, 600, 1400, 2100, 2300, 39260, 40260** to an eighth drilling mud manifold **39305, 40305**.

In an embodiment, the fifteenth cross-over connection **3105, 39495, 40495** may have an integral flange at a fifteenth drilling mud outlet.

In an embodiment, the eighth drilling mud manifold **39305, 40305** may have an integral flange at the eighth, first drilling mud inlet **39310a, 40310a**, the eighth, second drilling mud inlet **39310b, 40310b**, the eighth, third drilling mud inlet **39310c, 40310c**, the eighth, fourth drilling mud inlet **39310d, 40310d** and/or the eighth drilling mud outlet **39315, 40315**.

In an embodiment, the eighth drilling mud outlet **425, 625b, 1425, 2125b, 2325b, 39285, 40285** of the eighth drilling mud screen system **400, 600, 1400, 2100, 2300, 39275, 40275** and the eighth, fourth drilling mud inlet **39310d, 40310d** of the eighth drilling mud manifold **39305, 40305** may be fluidly connected by a connection. Any suitable connection may be used for the eighth drilling mud outlet **425, 625b, 1425, 2125b, 2325b, 39285, 40285** of the eighth drilling mud screen system **400, 600, 1300, 2100, 2300, 39275, 40275** and the eighth, fourth drilling mud inlet **39310d, 40310d** of the eighth drilling mud manifold **39305, 40305**. For example, suitable connections include, but are not limited to, flanges and pipe fittings. Connections are well known in the art.

In an embodiment, the flow loop configuration **3900, 4000** comprises a sixteenth cross-over connection **3105, 39500, 40500** from a eighth drilling mud screen system **400, 600, 1400, 2100, 2300, 39275, 40275** to an eighth drilling mud manifold **39305, 40305**.

In an embodiment, the sixteenth cross-over connection **3105, 39500, 40500** may have an integral flange at a sixteenth drilling mud outlet.

In an embodiment, the eighth drilling mud manifold **39305, 40305** may have an integral flange at the eighth, first drilling mud inlet **39310a, 40310a**, the eighth, second drill-

ing mud inlet **39310b, 40310b**, the eighth, third drilling mud inlet **39310c, 40310c**, the eighth, fourth drilling mud inlet **39310d, 40310d** and/or the eighth drilling mud outlet **39315, 40315**.

In an embodiment, the seventh drilling mud outlet **39300, 40300** of the seventh drilling mud manifold **39290, 40290** and the third drilling mud inlet **39325, 40325** of the third gate valve **39320, 40320** may be fluidly connected by a connection. Any suitable connection may be used for the seventh drilling mud outlet **39300, 40300** of the seventh drilling mud manifold **39290, 40290** and the third drilling mud inlet **39325, 40325** of the third gate valve **39320, 40320**. For example, suitable connections include, but are not limited to, flanges and pipe fittings. Connections are well known in the art.

In an embodiment, the seventh drilling mud manifold **39290, 40290** may have an integral flange at the seventh, first drilling mud inlet **39295a, 40295a**, the seventh, second drilling mud inlet **39295b, 40295b**, the seventh, third drilling mud inlet **39295c, 40295c**, the seventh, fourth drilling mud inlet **39295d, 40295d** and/or the seventh drilling mud outlet **39300, 40300**.

In an embodiment, the third gate valve **39320, 40320** may have an integral flange at the third drilling mud inlet **39325, 40325** and/or the third drilling mud outlet **39330, 40330**.

In an embodiment, the eighth drilling mud outlet **39315, 40315** of the eighth drilling mud manifold **39305, 40305** and the fourth drilling mud inlet **39340, 40340** of the fourth gate valve **39335, 40335** may be fluidly connected by a connection. Any suitable connection may be used for the eighth drilling mud outlet **39315, 40315** of the eighth drilling mud manifold **39305, 40305** and the fourth drilling mud inlet **39340, 40340** of the fourth gate valve **39335, 40335**. For example, suitable connections include, but are not limited to, flanges and pipe fittings. Connections are well known in the art.

In an embodiment, the eighth drilling mud manifold **39305, 40305** may have an integral flange at the eighth, first drilling mud inlet **39310a, 40310a**, the eighth, second drilling mud inlet **39310b, 40310b**, the eighth, third drilling mud inlet **39310c, 40310c**, the eighth, fourth drilling mud inlet **39310d, 40310d** and/or the eighth drilling mud outlet **39315, 40315**.

In an embodiment, the fourth gate valve **39335, 40335** may have an integral flange at the fourth drilling mud inlet **39340, 40340** and/or the fourth drilling mud outlet **39345, 40345**.

In an embodiment, the third drilling mud outlet **39330, 40330** of the third gate valve **39320, 40320** and the ninth, first drilling mud inlet **39355a, 40355a** of the ninth drilling mud manifold **39350, 40350** may be fluidly connected by a connection. Any suitable connection may be used for the third drilling mud outlet **39330, 40330** of the third gate valve **39320, 40320** and the ninth, first drilling mud inlet **39355a, 40355a** of the ninth drilling mud manifold **39350, 40350**. For example, suitable connections include, but are not limited to, flanges and pipe fittings. Connections are well known in the art.

In an embodiment, the third gate valve **39320, 40320** may have an integral flange at the third drilling mud inlet **39325, 40325** and/or the third drilling mud outlet **39330, 40330**.

In an embodiment, the ninth drilling mud manifold **39350, 40350** may have an integral flange at the ninth, first drilling mud inlet **39355a, 40355a**, the ninth, second drilling mud inlet **39355b, 40355b** and/or the ninth drilling mud outlet **39360, 40360**.

In an embodiment, the fourth drilling mud outlet **39345, 40345** of the fourth gate valve **39335, 40335** and the ninth, second drilling mud inlet **39355b, 40355b** of the ninth drilling mud manifold **39350, 40350** may be fluidly connected by a connection. Any suitable connection may be used for the fourth drilling mud outlet **39345, 40345** of the fourth gate valve **39335, 40335** and the ninth, second drilling mud inlet **39355b, 40355b** of the ninth drilling mud manifold **39350, 40350**. For example, suitable connections include, but are not limited to, flanges and pipe fittings. Connections are well known in the art.

In an embodiment, the fourth gate valve **39335, 40335** may have an integral flange at the fourth drilling mud inlet **39340, 40340** and/or the fourth drilling mud outlet **39345, 40345**.

In an embodiment, the ninth drilling mud manifold **39350, 40350** may have an integral flange at the ninth, first drilling mud inlet **39355a, 40355a**, the ninth, second drilling mud inlet **39355b, 40355b** and/or the ninth drilling mud outlet **39360, 40360**.

In an embodiment, the ninth drilling mud outlet **39360, 40360** of the ninth drilling mud manifold **39350, 40350** may be fluidly connected to a fourth spool **39365, 40365** via a connection. Any suitable connection may be used for the ninth drilling mud outlet **39360, 40360** of the ninth drilling mud manifold **39350, 40350** and the fourth spool **39365, 40365**. For example, suitable connections include, but are not limited to, flanges and pipe fittings. Connections are well known in the art.

In an embodiment, the ninth drilling mud manifold **39350, 40350** may have an integral flange at the ninth, first drilling mud inlet **39355a, 40355a**, the ninth, second drilling mud inlet **39355b, 40355b** and/or the ninth drilling mud outlet **39360, 40360**.

In an embodiment, the fourth spool **39365, 40365** may have an integral flange at a fourth drilling mud inlet **39370, 40370** and/or a fourth drilling mud outlet **39375, 40375**.

In an embodiment, the fourth spool **39365, 40365** and a tenth drilling mud inlet **39385, 40385** of a tenth drilling mud manifold **39380, 40380** may be fluidly connected via a connection. Any suitable connection may be used for the fourth spool **39365, 40365** and the tenth drilling mud inlet **39385, 40385** of the tenth drilling mud manifold **39380, 40380**. For example, suitable connections include, but are not limited to, flanges and pipe fittings. Connections are well known in the art.

In an embodiment, the fourth spool **39365, 40365** may have an integral flange at a fourth drilling mud inlet **39370, 40370** and/or a fourth drilling mud outlet **39375, 40375**.

In an embodiment, the tenth drilling mud manifold **39380, 40380** may have an integral flange at a tenth drilling mud inlet **39385, 40385** and/or a tenth drilling mud outlet **39390, 40390**.

In an embodiment, the tenth drilling mud outlet **39390, 40390** of the tenth drilling mud manifold **39380, 40380** and the fifth spool **39395, 40395** may be fluidly connected via a connection. Any suitable connection may be used for the tenth drilling mud outlet **39390, 40390** of the tenth drilling mud manifold **39380, 40380** and the fifth spool **39395, 40395**. For example, suitable connections include, but are not limited to, flanges and pipe fittings. Connections are well known in the art.

In an embodiment, the tenth drilling mud manifold **39380, 40380** may have an integral flange at a tenth drilling mud inlet **39385, 40385** and/or a tenth drilling mud outlet **39390, 40390**.

127

In an embodiment, the fifth spool 39395, 40395 may have an integral flange at a fifth drilling mud inlet 39400, 40400 and/or a fifth drilling mud outlet 39405, 40405.

In an embodiment, the fifth spool 39395, 40395 and an eleventh drilling mud inlet 39415, 40415 of an eleventh drilling mud manifold 39410, 40410 may be fluidly connected via a connector. Any suitable connector may be used for the fifth spool 39395, 40395 and the eleventh drilling mud inlet 39415, 40415 of the eleventh drilling mud manifold 39410, 40410. For example, suitable connections include, but are not limited to, flanges and pipe fittings. Connections are well known in the art.

In an embodiment, the fifth spool 39395, 40395 may have an integral flange at a fifth drilling mud inlet 39400, 40400 and/or a fifth drilling mud outlet 39405, 40405.

In an embodiment, the eleventh drilling mud manifold 39410, 40410 may have an integral flange at an eleventh drilling mud inlet 39415, 40415 and/or an eleventh drilling mud outlet 39420, 40420.

Drilling Mud Screen Puller/Installer Tool

FIGS. 8A-8B and 9A-9B illustrate a drilling mud screen puller/installer tool according to an embodiment of the present invention. The tool permits use of a deep bore in a single-piece body of the drilling mud screen system, and removal of the drilling mud screen from the two-piece body without disassembly of the two-piece body. Further, the tool provides additional force to remove "stuck" drilling mud screens from debris entrapment in the system.

Single-Piece Body

FIG. 8A illustrates an upper cross-sectional view of a drilling mud screen puller/installer tool for the exemplary drilling mud screen system of FIGS. 4A-4C; and FIGS. 18A-18B illustrate an upper cross-sectional view of the drilling mud screen puller/installer tool of FIG. 8A for the exemplary drilling mud system of FIGS. 4A-4C and 14.

As shown in FIG. 8A, the drilling mud screen puller/installer tool 800 has a body 805 having a first end 810 and a second end 815 and a first length 820, a shaft 825 having a first end 830 and a second end 835 and a second length 840, a movable sleeve 845 having a first end 850 and a second end 855 and a third length 860, a handle 865, and a puller/installer plate 870.

The first length 820 of the body 805 may be any suitable length. In an embodiment, the first length 820 of the body 805 may be from about 10-inches to about 30-inches, and any range or value there between. In an embodiment, the first length 820 of the body 805 may be from about 18-inches to about 22-inches.

The inner diameter of the body 805 may be any suitable diameter. In an embodiment, the inner diameter of the body 805 may be from about 1-inch to about 2-inches, and any range or value there between. In an embodiment, the inner diameter of the body 805 may be about 1.5-inches.

The outer diameter of the body 805 may be any suitable diameter. In an embodiment, the outer diameter of the body 805 may be from about 1.5-inches to about 2.5-inches, and any range or value there between. In an embodiment, the outer diameter of the body 805 may be about 1.9-inches.

In an embodiment, the body 805 of the drilling mud screen puller/installer tool 800 may be constructed of any suitable material. For example, suitable materials include, but are not limited to, any alloy steel. In an embodiment, the body 805 may be constructed of an American Iron and Steel Industry (AISI) 4140 or equivalent material, stainless steel and combinations thereof. See e.g., FIG. 8A. In an embodiment, the surface of the body 805 may be painted.

128

In an embodiment, the body 805 may have a first striker plate 8100.

The striker plate 8100 may be any suitable length. In an embodiment, the length of the striker plate 8100 may be from about 0.3-inches to about 0.6-inches, and any range or value there between. In an embodiment, the length of the striker plate 8100 may be about 0.5-inches.

In an embodiment, the inner diameter of the striker plate 8100 may be any suitable diameter. In an embodiment, the inner diameter of the striker plate 8100 may be from about 1-inch to about 1.25-inches, and any range or value there between. In an embodiment, the inner diameter of the striker plate 8100 may be about 1.13-inches.

In an embodiment, the outer diameter of the striker plate 8100 may be any suitable diameter. In an embodiment, the outer diameter of the striker plate 8100 may be from about 2-inches to about 2.25-inches, and any range or value there between. In an embodiment, the outer diameter of the striker plate 8100 may be about 2.130-inches.

In an embodiment, the striker plate 8100 of the drilling mud screen puller/installer tool 800 may be constructed of any suitable material. For example, suitable materials include, but are not limited to, any alloy steel. In an embodiment, the striker plate 8100 may be constructed of stainless steel. See e.g., FIG. 8A. In an embodiment, the surface of the striker plate 8100 may be painted.

In an embodiment, the striker plate 8100 may be attached to the second end 815 of the body 805 via a connection. Any suitable connection may be used for the striker plate 8100. For example, suitable connections include, but are not limited to, pipe fittings and welds. Connections are well known in the art. In an embodiment, the striker plate 8100 may be attached to the second end 815 of the body 805 via a weld.

In an embodiment, the second length 840 of the shaft 825 may be any suitable length. In an embodiment, the second length 840 of the shaft 825 may be from about 30-inches to about 50-inches, and any range or value there between. In an embodiment, the second length 840 of the shaft 825 may be from about 40-inches to about 42-inches.

The diameter of the shaft 825 may be any suitable diameter. In an embodiment, the diameter of the shaft 825 may be from about 0.75-inches to about 1.5-inches, and any range or value there between. In an embodiment, the diameter of the shaft 825 may be about 1.1-inches.

In an embodiment, the shaft 825 of the drilling mud screen puller/installer tool 800 may be constructed of any suitable material. For example, suitable materials include, but are not limited to, any alloy steel. In an embodiment, the shaft 825 may be constructed of an American Iron and Steel Industry (AISI) 1018 or equivalent material. See e.g., FIG. 8A. In an embodiment, the surface of the shaft 825 may be painted.

In an embodiment, the third length 860 of the movable sleeve 845 may be any suitable length. In an embodiment, the third length 860 of the movable sleeve 845 may be from about 10-inches to about 30-inches, and any range or value there between. In an embodiment, the third length 860 of the movable sleeve 845 may be from about 20-inches to about 22-inches.

The inner diameter of the movable sleeve 845 may be any suitable diameter. In an embodiment, the inner diameter of the movable sleeve 845 may be from about 1-inch to about 2-inches, and any range or value there between. In an embodiment, the inner diameter of the movable sleeve 845 may be about 1.4-inches.

The outer diameter of the movable sleeve 845 may be any suitable diameter. In an embodiment, the outer diameter of the movable sleeve 845 may be from about 1.5-inches to about 2.5-inches, and any range or value there between. In an embodiment, the outer diameter of the movable sleeve 845 may be about 1.9-inches.

In an embodiment, the movable sleeve 845 of the drilling mud screen puller/installer tool 800 may be constructed of any suitable material. For example, suitable materials include, but are not limited to, any alloy steel. In an embodiment, the movable sleeve 845 may be constructed of an American Iron and Steel Industry (AISI) 4140 or equivalent material. See e.g., FIG. 8A. In an embodiment, the surface of the movable sleeve 845 may be painted.

In an embodiment, the first end 810 of the body 805 may have a rounded end 875 having a first end and a second end; the second end 815 of the body 805 may have a striker plate 8100.

The length of the rounded end 875 may be any suitable length. In an embodiment, the length of the rounded end 875 may be from about 1-inch to about 2-inches, and any range or value there between. In an embodiment, the length of the rounded end 875 may be about 1.3-inches.

The inner diameter of the rounded end 875 may be any suitable diameter. In an embodiment, the inner diameter of the rounded end 875 may be from about 1.5-inches to about 2-inches, and any range or value there between. In an embodiment, the inner diameter of the rounded end 875 may be about 1.7-inches.

The outer diameter of the rounded end 875 may be any suitable diameter. In an embodiment, the outer diameter of the rounded end 875 may be from about 2.5-inches to about 3.5-inches, and any range or value there between. In an embodiment, the outer diameter of the rounded end 875 may be about 3-inches.

In an embodiment, the first end of the rounded end 875 may have a rounded edge. See e.g., FIG. 8. The radius of the rounded edge may be any suitable radius. In an embodiment, the radius may be from about 0.35-inches to about 0.4-inches, and any range or value there between. In an embodiment, the radius may be about 0.375-inches.

In an embodiment, the rounded end 875 of the drilling mud screen puller/installer tool 800 may be constructed of any suitable material. For example, suitable materials include, but are not limited to, any alloy steel. In an embodiment, the rounded end 875 may be painted.

In an embodiment, the second end of the rounded end 875 may be attached to the first end 810 of the body 805 via a connection. Any suitable connection may be used for the second end of the rounded end 875. For example, suitable connections include, but are not limited to, pipe fittings and welds. Connections are well known in the art. In an embodiment, the second end of the rounded end 875 may be attached to the first end 810 of the body 805 via a weld.

In an embodiment, the body 805 may have a sleeve body 880 having a first end 885 and a second end 890 and a fourth length 895, and a first striker plate 8100.

The fourth length 895 of the sleeve body 880 may be any suitable length. In an embodiment, the fourth length 895 of the sleeve body 880 may be from about 10-inches to about 40-inches, and any range or value there between. In an embodiment, the fourth length 895 of the sleeve body 880 may be from about 20-inches to about 22-inches.

The inner diameter of the sleeve body 880 may be any suitable diameter. In an embodiment, the inner diameter of the sleeve body 880 may be from about 1-inch to about

2-inches, and any range or value there between. In an embodiment, the inner diameter of the sleeve body 880 may be about 1.4-inches.

The outer diameter of the sleeve body 880 may be any suitable diameter. In an embodiment, the outer diameter of the sleeve body 880 may be from about 1.5-inches to about 2.5-inches, and any range or value there between. In an embodiment, the outer diameter of the sleeve body 880 may be about 1.9-inches.

10 In an embodiment, the sleeve body 880 of the drilling mud screen puller/installer tool 800 may be constructed of any suitable material. For example, suitable materials include, but are not limited to, any alloy steel. In an embodiment, the sleeve body 880 may be constructed of an 15 American Iron and Steel Industry (AISI) 4140 or equivalent material, stainless steel and combinations thereof. See e.g., FIG. 8A. In an embodiment, the surface of the sleeve body 880 may be painted.

In an embodiment, the rounded end 875 may be attached 20 to the first end 885 of the sleeve body 880 via a connection. Any suitable connection may be used for the rounded end 875. For example, suitable connections include, but are not limited to, pipe fittings and welds. Connections are well known in the art. In an embodiment, the rounded end 875 may be attached to the first end 885 of the sleeve body 880 via a weld.

In an embodiment, the striker plate 8100 may be attached 25 to the second end 890 of the sleeve body 880 via a connection. Any suitable connection may be used for the the 30 striker plate 8100. For example, suitable connections include, but are not limited to, pipe fittings and welds. Connections are well known in the art. In an embodiment, the striker plate 8100 may be attached to the second end 890 of the sleeve body 880 via a weld.

35 In an embodiment, the second end 815 of the body 805 may be attached to the first end 830 of the shaft 825 via a connection. Any suitable connection may be used for the second end 815 of the body 805. For example, suitable connections include, but are not limited to, pipe fittings and 40 welds. Connections are well known in the art. In an embodiment, the second end 815 of the body 805 may be attached to the first end 830 of the shaft 825 via a weld.

In an embodiment, the movable sleeve 845 may be disposed around the shaft 825.

45 In an embodiment, a handle 865 may be attached to the movable sleeve 845 via a connection. Any suitable connection may be used for the handle 865. For example, suitable connections include, but are not limited to, pipe fittings and welds. Connections are well known in the art. In an embodiment, the handle 865 may be attached to the movable sleeve 845 via a weld.

The handle 865 may be any suitable handle to move the moveable sleeve 845 back and forth. Suitable handles 865 include, but are not limited to, one or more hand holds 55 extending from the movable sleeve 845, a hand ring or hand wheel surrounding the movable sleeve 845, and combinations thereof.

The diameter of the one or more hand holds of the handle 865 may be any suitable diameter. In an embodiment, the diameter of the one or more hand holds of the handle 865 may be from 0.3-inch to about 1.0-inch, and any range or value there between. In an embodiment, the diameter of the one or more hand holds of the handle 865 may be about 0.5-inch.

60 In an embodiment, the handle 865 of the drilling mud screen puller/installer tool 800 may be constructed of any suitable material. For example, suitable materials include,

131

but are not limited to, any alloy steel. In an embodiment, the handle 865 may be constructed of an American Iron and Steel Industry (AISI) 1018 or equivalent material. See e.g., FIG. 8A. In an embodiment, the surface of the handle 865 may be painted.

In an embodiment, the handle 865 may be attached to the movable sleeve 845 via a connection. Any suitable connection may be used for the handle 865. For example, suitable connections include, but are not limited to, pipe fittings and welds. Connections are well known in the art. In an embodiment, the handle 865 may be attached to the movable sleeve 845 via a weld.

In an embodiment, the puller/installer plate 870 may be attached to a second end 835 of the shaft 825 via a connection. Any suitable connection may be used for the puller/installer plate 870. For example, suitable connections include, but are not limited to, pipe fittings and welds. Connections are well known in the art. In an embodiment, the puller/installer plate 870 may be attached to the second end 835 of the shaft 825 via a weld.

The length of the puller/installer plate 870 may be any suitable length. In an embodiment, the length of the puller/installer plate 870 may be from about 0.5-inch to about 1-inch, and any range or value there between. In an embodiment, the length of the puller/installer plate 870 may be about 0.725-inch.

The diameter of the puller/installer plate 870 may be any suitable diameter. In an embodiment, the diameter of the puller/installer plate 870 may be from about 2-inches to about 2.5-inches, and any range or value there between. In an embodiment, the diameter of the puller/installer plate 870 may be about 2.3-inches.

In an embodiment, the puller/installer plate 870 of the drilling mud screen puller/installer tool 800 may be constructed of any suitable material. For example, suitable materials include, but are not limited to, any alloy steel. In an embodiment, the puller/installer plate 870 may be constructed of a stainless steel. See e.g., FIG. 8A. In an embodiment, the surface of the puller/installer plate 870 may be painted.

In an embodiment, the puller/installer plate 870 may have a means to engage 8105 a drilling mud screen 500 of the drilling mud screen system 400. The means to engage 875 may be any suitable means to engage 8105 the drilling mud screen 500. For example, a suitable means to engage 8105 includes, but is not limited to, one or more extensions to fit an outlet of the first portion 575 and/or an inlet of the second portion 580 of the body 505 of the drilling mud screen 500 and to engage a shoulder outside the inlet of the second portion 580 of the body 505 of the drilling mud screen 500 and/or to rotationally engage a shoulder inside the inlet of the second portion 580 of the body 505 of the drilling mud screen 500. Cf. FIGS. 5B & 8B. See also FIGS. 12A-12B. In an embodiment, the puller/installer plate 870 may have one or more extensions to fit an outlet of the first portion 575 and/or an inlet of the second portion 580 of the body 505 of the drilling mud screen 500 and to engage a shoulder outside the inlet of the second portion 580 of the body 505 of the drilling mud screen 500 and/or to rotationally engage a shoulder inside the inlet of the second portion 580 of the body 505 of the drilling mud screen 500. Id.

In an embodiment, the means to engage 8105 may be constructed of any suitable material. For example, suitable materials include, but are not limited to, any alloy steel. In an embodiment, the means to engage 8105 may be con-

132

structed of a stainless steel or equivalent material. See e.g., FIG. 8A. In an embodiment, the means to engage 8105 may be painted.

Two-Piece Body

FIG. 9A illustrates an upper cross-sectional view of a drilling mud screen puller/installer tool for the exemplary drilling mud screen system of FIG. 7. As shown in FIG. 9, the drilling mud screen puller/installer tool 900 has a body 905 having a first end 910 and a second end 915 and a first length 920, a shaft 925 having a first end 930 and a second end 935 and a second length 940, a movable sleeve 945 having a first end 950 and a second end 955 and a third length 960, a handle 965, and a puller/installer plate 970.

The first length 920 of the body 905 may be any suitable length. In an embodiment, the first length 920 of the body 905 may be from about 10-inches to about 30-inches, and any range or value there between. In an embodiment, the first length 920 of the body 905 may be from about 18-inches to about 22-inches.

The inner diameter inner diameter of the body 905 may be any suitable diameter. In an embodiment, the inner diameter of the body 905 may be from about 1-inch to about 2-inches, and any range or value there between. In an embodiment, the inner diameter of the body 905 may be about 1.5-inches.

The outer diameter of the body 905 may be any suitable diameter. In an embodiment, the outer diameter of the body 905 may be from about 1.5-inches to about 2.5-inches, and any range or value there between. In an embodiment, the outer diameter of the body 905 may be about 1.9-inches.

In an embodiment, the body 905 of the drilling mud screen puller/installer tool 900 may be constructed of any suitable material. For example, suitable materials include, but are not limited to, any alloy steel. In an embodiment, the body 905 may be constructed of an American Iron and Steel Industry (AISI) 4140 or equivalent material, stainless steel and combinations thereof. See e.g., FIG. 9A. In an embodiment, the surface of the body 905 may be painted.

In an embodiment, the body 905 may have a striker plate 9100.

The striker plate 9100 may be any suitable length. In an embodiment, the length of the striker plate 9100 may be from about 0.3-inch to about 0.6-inch, and any range or value there between. In an embodiment, the length of the striker plate 9100 may be about 0.5-inch.

In an embodiment, the inner diameter of the striker plate 9100 may be any suitable diameter. In an embodiment, the inner diameter of the striker plate 9100 may be from about 1-inch to about 1.25-inches, and any range or value there between. In an embodiment, the inner diameter of the striker plate 9100 may be about 1.13-inches.

In an embodiment, the outer diameter of the striker plate 9100 may be any suitable diameter. In an embodiment, the outer diameter of the striker plate 9100 may be from about 2-inches to about 2.25-inches, and any range or value there between. In an embodiment, the outer diameter of the striker plate 9100 may be about 2.130-inches.

In an embodiment, the striker plate 9100 of the drilling mud screen puller/installer tool 900 may be constructed of any suitable material. For example, suitable materials include, but are not limited to, any alloy steel. In an embodiment, the striker plate 9100 may be constructed of stainless steel. See e.g., FIG. 9A. In an embodiment, the surface of the striker plate 9100 may be painted.

In an embodiment, the striker plate 9100 may be attached to the second end 915 of the body 905 via a connection. Any suitable connection may be used for the striker plate 9100. For example, suitable connections include, but are not

133

limited to, pipe fittings and welds. Connections are well known in the art. In an embodiment, the striker plate 9100 may be attached to the second end 915 of the body 905 via a weld.

In an embodiment, the second length 940 of the shaft 925 may be any suitable length. In an embodiment, the second length 940 of the shaft 925 may be from about 40-inches to about 60-inches, and any range or value there between. In an embodiment, the second length 940 of the shaft 925 may be from about 50-inches to about 52-inches.

The diameter of the shaft 925 may be any suitable diameter. In an embodiment, the diameter of the shaft 925 may be from about 0.75-inch to about 1.5-inches, and any range or value there between. In an embodiment, the diameter of the shaft 925 may be about 1.1-inches.

In an embodiment, the shaft 925 of the drilling mud screen puller/installer tool 900 may be constructed of any suitable material. For example, suitable materials include, but are not limited to, any alloy steel. In an embodiment, the shaft 925 may be constructed of an American Iron and Steel Industry (AISI) 1018 or equivalent material. See e.g., FIG. 9A. In an embodiment, the surface of the shaft 925 may be painted.

In an embodiment, the third length 960 of the movable sleeve 945 may be any suitable length. In an embodiment, the third length 960 of the movable sleeve 945 may be from about 10-inches to about 30-inches, and any range or value there between. In an embodiment, the third length 960 of the movable sleeve 945 may be from about 20-inches to about 22-inches.

The inner diameter of the movable sleeve 945 may be any suitable diameter. In an embodiment, the inner diameter of the movable sleeve 945 may be from about 1-inch to about 2-inches, and any range or value there between. In an embodiment, the inner diameter of the movable sleeve 945 may be about 1.4-inches.

The outer diameter of the movable sleeve 945 may be any suitable diameter. In an embodiment, the outer diameter of the movable sleeve 945 may be from about 1.5-inches to about 2.5-inches, and any range or value there between. In an embodiment, the outer diameter of the movable sleeve 945 may be about 1.9-inches.

In an embodiment, the movable sleeve 945 of the drilling mud screen puller/installer tool 900 may be constructed of any suitable material. For example, suitable materials include, but are not limited to, any alloy steel. In an embodiment, the movable sleeve 945 may be constructed of an American Iron and Steel Industry (AISI) 4140 or equivalent material. See e.g., FIG. 9A. In an embodiment, the surface of the movable sleeve 945 may be painted.

In an embodiment, the first end 910 of the body 905 may have a rounded end 975 having a first end and a second end; the second end 915 of the body 905 may have a striker plate 9100.

The length of the rounded end 975 may be any suitable length. In an embodiment, the length of the rounded end 975 may be from about 1-inch to about 2-inches, and any range or value there between. In an embodiment, the length of the rounded end 975 may be about 1.3-inches.

The inner diameter of the rounded end 975 may be any suitable diameter. In an embodiment, the inner diameter of the rounded end 975 may be from about 1.5-inches to about 2-inches, and any range or value there between. In an embodiment, the inner diameter of the rounded end 975 may be about 1.7-inches.

The outer diameter of the rounded end 975 may be any suitable diameter. In an embodiment, the outer diameter of

134

the rounded end 975 may be from about 2.5-inches to about 3.5-inches, and any range or value there between. In an embodiment, the outer diameter of the rounded end 975 may be about 3-inches.

5 In an embodiment, the first end of the rounded end 975 may have a rounded edge. See e.g., FIG. 9A. The radius of the rounded edge may be any suitable radius. In an embodiment, the radius may be from about 0.35-inch to about 0.4-inch, and any range or value there between. In an

10 embodiment, the radius may be about 0.375-inch.

In an embodiment, the rounded end 975 of the drilling mud screen puller/installer tool 900 may be constructed of any suitable material. For example, suitable materials include, but are not limited to, any alloy steel. In an embodiment, the rounded end 975 may be painted.

15 In an embodiment, the second end of the rounded end 975 may be attached to the first end 910 of the body 905 via a connection. Any suitable connection may be used for the second end of the rounded end 975. For example, suitable 20 connections include, but are not limited to, pipe fittings and welds. Connections are well known in the art. In an embodiment, the second end of the rounded end 975 may be attached to the first end 910 of the body 905 via a weld.

In an embodiment, the body 905 may have a sleeve body 25 980 having a first end 985 and a second end 990 and a fourth length 995, and a striker plate 9100.

The fourth length 995 of the sleeve body 980 may be any suitable length. In an embodiment, the fourth length 995 of the sleeve body 980 may be from about 10-inches to about 30 40-inches, and any range or value there between. In an embodiment, the fourth length 995 of the sleeve body 980 may be from about 18-inches to about 20-inches.

35 The inner diameter of the sleeve body 980 may be any suitable diameter. In an embodiment, the inner diameter of the sleeve body 980 may be from about 1-inch to about 2-inches, and any range or value there between. In an embodiment, the inner diameter of the sleeve body 980 may be about 1.4-inches.

The outer diameter of the sleeve body 980 may be any 40 suitable diameter. In an embodiment, the outer diameter of the sleeve body 980 may be from about 1.5-inches to about 2.5-inches, and any range or value there between. In an embodiment, the outer diameter of the sleeve body 980 may be about 1.9-inches.

45 In an embodiment, the sleeve body 980 of the drilling mud screen puller/installer tool 900 may be constructed of any suitable material. For example, suitable materials include, but are not limited to, any alloy steel. In an embodiment, the sleeve body 980 may be constructed of an

50 American Iron and Steel Industry (AISI) 4140 or equivalent material, stainless steel and combinations thereof. See e.g., FIG. 9A. In an embodiment, the surface of the sleeve body 980 may be painted.

In an embodiment, the rounded end 975 may be attached 55 to the first end 985 of the sleeve body 880 via a connection. Any suitable connection may be used for the rounded end 975. For example, suitable connections include, but are not limited to, pipe fittings and welds. Connections are well known in the art. In an embodiment, the rounded end 975 may be attached to the first end 985 of the sleeve body 980 via a weld.

In an embodiment, the striker plate 9100 may be attached 60 to the second end 990 of the sleeve body 980 via a connection. Any suitable connection may be used for the 65 striker plate 9100. For example, suitable connections include, but are not limited to, pipe fittings and welds. Connections are well known in the art. In an embodiment,

135

the striker plate 9100 may be attached to the second end 990 of the sleeve body 980 via a weld.

In an embodiment, the second end 915 of the body 905 may be attached to the first end 930 of the shaft 925 via a connection. Any suitable connection may be used for the second end 915 of the body 905. For example, suitable connections include, but are not limited to, pipe fittings and welds. Connections are well known in the art. In an embodiment, the second end 915 of the body 905 may be attached to the first end 930 of the shaft 925 via a weld.

In an embodiment, the movable sleeve 945 may be disposed around the shaft 925.

In an embodiment, a handle 965 may be attached to the movable sleeve 945 via a connection. Any suitable connection may be used for the handle 965. For example, suitable connections include, but are not limited to, pipe fittings and welds. Connections are well known in the art. In an embodiment, the handle 965 may be attached to the movable sleeve 945 via a weld.

The handle 965 may be any suitable handle to move the moveable sleeve 945 back and forth. For example, suitable handles 965 include, but are not limited to, one or more hand holds extending from the movable sleeve 945, a hand ring or hand wheel surrounding the movable sleeve 945, and combinations thereof.

The diameter of the one or more hand holds of the handle 965 may be any suitable diameter. In an embodiment, the diameter of the one or more hand holds of the handle 965 may be from 0.3-inch to about 1.0-inch, and any range or value there between. In an embodiment, the diameter of the one or more hand holds of the handle 965 may be about 0.5-inch.

In an embodiment, the handle 965 of the drilling mud screen puller/installer tool 900 may be constructed of any suitable material. For example, suitable materials include, but are not limited to, any alloy steel. In an embodiment, the handle 965 may be constructed of an American Iron and Steel Industry (AISI) 1018 or equivalent material. See e.g., FIG. 9A. In an embodiment, the surface of the handle 965 may be painted.

In an embodiment, the handle 965 may be attached to the movable sleeve 945 via a connection. Any suitable connection may be used for the handle 965. For example, suitable connections include, but are not limited to, pipe fittings and welds. Connections are well known in the art. In an embodiment, the handle 965 may be attached to the movable sleeve 945 via a weld.

In an embodiment, the puller/installer plate 970 may be attached to a second end 935 of the shaft 925 via a connection. Any suitable connection may be used for the puller/installer plate 970. For example, suitable connections include, but are not limited to, pipe fittings and welds. Connections are well known in the art. In an embodiment, the puller/installer plate 970 may be attached to the second end 935 of the shaft 925 via a weld.

The length of the puller/installer plate 970 may be any suitable length. In an embodiment, the length of the puller/installer plate 970 may be from about 0.5-inch to about 1-inch, and any range or value there between. In an embodiment, the length of the puller/installer plate 970 may be about 0.725-inch.

The diameter of the puller/installer plate 970 may be any suitable diameter. In an embodiment, the diameter of the puller/installer plate 970 may be from about 2-inches to about 2.5-inches, and any range or value there between. In an embodiment, the diameter of the puller/installer plate 970 may be about 2.3-inches.

136

In an embodiment, the puller/installer plate 970 of the drilling mud screen puller/installer tool 900 may be constructed of any suitable material. For example, suitable materials include, but are not limited to, any alloy steel. In an embodiment, the puller/installer plate 970 may be constructed of a stainless steel. See e.g., FIG. 9A. In an embodiment, the surface of the puller/installer plate 970 may be painted.

In an embodiment, the puller/installer plate 970 may have 10 a means to engage 9105 a drilling mud screen 500 of the drilling mud screen system 400. The means to engage 975 may be any suitable means to engage 9105 the drilling mud screen 500. For example, a suitable means to engage 9105 includes, but is not limited to, one or more extensions to fit 15 an outlet of the first portion 575 and/or an inlet of the second portion 580 of the body 505 of the drilling mud screen 500 and to engage a shoulder outside the inlet of the second portion 580 of the body 505 of the drilling mud screen 500 and/or to rotationally engage a shoulder inside the inlet of the second portion 580 of the body 505 of the drilling mud screen 500. Cf. FIGS. 5B & 8B. See also FIGS. 13A-13B. In an embodiment, the puller/installer plate 970 may have one or more extensions to fit an outlet of the first portion 575 and/or an inlet of the second portion 580 of the body 505 of 25 the drilling mud screen 500 and to engage a shoulder outside the inlet of the second portion 580 of the body 505 of the drilling mud screen 500 and/or to rotationally engage a shoulder inside the inlet of the second portion 580 of the body 505 of the drilling mud screen 500. Id.

In an embodiment, the means to engage 9105 may be 30 constructed of any suitable material. For example, suitable materials include, but are not limited to, any alloy steel. In an embodiment, the means to engage 9105 may be constructed of a stainless steel or equivalent material. See e.g., FIG. 9A. In an embodiment, the means to engage 9105 may be painted.

Optional Drilling Mud Screen Installer/Puller Tool
Single-Piece Body

In an embodiment, the drilling mud screen puller/installer 40 tool 800 has a body 805 having a first end 810 and a second end 815 and a first length 820, a shaft 825 having a first end 830 and a second end 835 and a second length 840, a movable sleeve 845 having a first end 850 and a second end 855 and a third length 860, a handle 865, an optional stop 45 plate (not shown) and a puller/installer plate 870. Cf. FIG. 29. In an embodiment, the optional stop plate (not shown) on the shaft 825 of the puller/installer tool 800 indicates that the puller/installer tool 800 (and, therefore, the drilling mud screen 500) is fully inserted into the drilling mud screen system 800 when the optional stop plate (not shown) contacts the first end 810 of the body 805 of the system 800.

In an embodiment, an optional groove or painted line may be used instead of the optional stop plate on the shaft 825 of the puller/installer tool 800. In an embodiment, the optional 55 groove or painted line (not shown) on the shaft 825 of the puller/installer tool 800 indicates that the puller/installer tool 800 (and, therefore, the drilling mud screen 500) is fully inserted into the drilling mud screen system 800 when the optional groove or painted line (not shown) lines up with the first end 810 of the body 805 of the system 800.

Two-Piece Body

FIG. 29 illustrates a cross-sectional view of the exemplary drilling mud tool of FIG. 9A inserting the drilling mud screen of FIG. 5 or 22 into the exemplary drilling mud screen system of FIG. 7A or 21B, showing an optional stop plate. As shown in FIG. 29, the drilling mud screen puller/installer tool 900 has a body 905 having a first end 910 and

a second end 915 and a first length 920, a shaft 925 having a first end 930 and a second end 935 and a second length 940, a movable sleeve 945 having a first end 950 and a second end 955 and a third length 960, a handle 965, an optional stop plate 29400 and a puller/installer plate 970. In an embodiment, the optional stop plate 29400 on the shaft 925 of the puller/installer tool 900 indicates that the puller/installer tool 900 (and, therefore, the drilling mud screen 500 or 2200) is fully inserted into the drilling mud screen system 700 or 2100 when the optional stop plate 29400 contacts the first end 710a or 2110a of the first body 705a or 2105a of the system 700 or 2100.

In an embodiment, an optional groove or painted line may be used instead of the optional stop plate 29400 on the shaft 925 of the puller/installer tool 900. In an embodiment, the optional groove or painted line (not shown) on the shaft 925 of the puller/installer tool 900 indicates that the puller/installer tool 900 (and, therefore, the drilling mud screen 500 or 2200) is fully inserted into the drilling mud screen system 700 or 2100 when the optional groove or painted line (not shown) lines up with the first end 710a or 2110a of the first body 705a or 2105a of the system 700 or 2100.

Method of Using Drilling Mud Screen System

FIG. 10 illustrates a flow diagram for a method of using a drilling mud screen system, as discussed above. As shown in FIG. 10, the method of using a drilling mud screen system 1000 comprises stopping a drilling mud pump to stop flow of drilling mud 1005, fluidly connecting a drilling mud inlet of a drilling mud screen system downstream of an outlet to the drilling mud pump 1010, fluidly connecting a drilling mud outlet of the drilling mud screen system upstream of an outlet of a stand pipe 1015, and starting the drilling mud pump to flow drilling mud through the drilling mud screen system 1020.

In an embodiment, the drilling mud inlet 120, 220, 320, 400, 620, 720, 3020 of the drilling mud screen system 100, 200, 300, 400, 600, 700, 3000 may be fluidly connected to a high pressure outlet of the drilling mud pump via a connection. See also FIGS. 14, 19, 21, 23 & 26. The inlet pressure to the drilling mud inlet 120, 220, 320, 400, 620, 720, 3020 of the drilling mud screen system 100, 200, 300, 400, 600, 700, 3000 may be any suitable pressure. In an embodiment, the inlet pressure may be from about 7500 psi to about 10,000 psi, and any range or value there between.

In an embodiment, the drilling mud outlet 125, 225, 325, 425, 625, 725, 3025 of the drilling mud screen system 100, 200, 300, 400, 600, 700, 3000 may be fluidly connected to an inlet of a vibrator hose to the standpipe via a connection.

In an embodiment, the drilling mud inlet 120, 220, 320, 400, 620, 720, 3020 of the drilling mud screen system 100, 200, 300, 400, 600, 700, 3000 may be fluidly connected to an outlet of a vibrator hose to a standpipe via a connection. In an embodiment, the drilling mud outlet 125, 225, 325, 425, 625, 725, 3025 of the drilling mud screen system 100, 200, 300, 400, 600, 700, 3000 may be fluidly connected to an inlet of the standpipe via a connection.

In an embodiment, the drilling mud screen system 100, 200, 300, 400, 600, 700, 3000 may be fluidly connected at any point in the standpipe via a connection.

Optional Monitoring Configuration

FIG. 10 illustrates a flow diagram for a method of using a drilling mud screen system, as discussed above. As shown in FIG. 10, the method of using a drilling mud screen system 1000 comprises stopping a drilling mud pump to stop flow of drilling mud 1005, fluidly connecting a drilling mud inlet of a drilling mud screen system downstream of an outlet to the drilling mud pump 1010, fluidly connecting a drilling

mud outlet of the drilling mud screen system upstream of an outlet of a stand pipe 1015, and starting the drilling mud pump to flow drilling mud through the drilling mud screen system 1020.

5 In an embodiment, step 1010 comprises fluidly connecting a drilling mud inlet of a transducer subassembly downstream of an outlet to the drilling mud pump; and fluidly connecting a drilling mud inlet of a drilling mud screen system downstream of a drilling mud outlet to the transducer subassembly.

10 As shown in FIGS. 19 and 28, the drilling mud inlet 1920 of the drilling mud screen system 19200, 28200 may be fluidly connected to a drilling mud outlet 28125 of the transducer subassembly 19110, 28100 via a connection. Any 15 suitable connection may be used for the drilling mud inlet 1920 and the drilling mud outlet 28125. For example, suitable connections include, but are not limited to, pipe fittings and welds. Connections are well known in the art. In an embodiment, the drilling mud inlet 1920 of the drilling 20 mud screen system 19200, 28200 may be fluidly connected to a drilling mud outlet 28125 of a transducer subassembly 19100 via a weld.

25 In an embodiment, the method of using a drilling mud screen system 1000 further comprises monitoring a transducer of the transducer subassembly for property information (e.g., displacement, flow rate, pressure, and/or temperature) at the drilling mud screen system.

30 In an embodiment, a computing device (such as a rig computer) may include a bus that directly or indirectly couples the following devices: memory, one or more processors, one or more presentation components, one or more input/output (I/O) ports, I/O components, a user interface and a power supply. The computing device may include a variety of computer-readable media. The memory may 35 include computer-storage media in the form of volatile and/or nonvolatile memory. The presentation component(s) present data indications to a user or other device. The user interface allows the user to input/output information to/from the computing device. The one or more I/O ports may allow the computing device to be logically coupled to other devices including a transducer 28105, and other I/O components, some of which may be built in. See e.g., FIG. 28. 40 Examples of other I/O components include a printer, scanner, wireless device, and the like.

45 In an embodiment, the method of using a drilling mud screen system 1000 further comprises using the property information (e.g., displacement, flow rate, pressure, and/or temperature) from the transducer of the transducer subassembly to determine a status of the drilling mud screen system. In an embodiment, the method further comprises using the information to determine when to clean, repair or replace the drilling mud screen in the drilling mud screen system.

50 In an embodiment, pressure information from, for example, a pressure transducer 28105 will allow a driller to know when a drilling mud screen 1940 in a drilling mud screen system 19200, 28200 is “packing off.” For example, the pressure information from the pressure transducer 28105 at the drilling mud inlet 1920 of the drilling mud screen system 19200, 28200 may be compared to, for example, 55 pressure information from a pressure transducer on a pressure transducer for a stand pipe. If the pressure decreases at the stand pipe and the pressure increases at the drilling mud inlet 1920 of the drilling mud screen system 19200, 28200, the drilling mud screen 1940 is likely “packing off” If the pressure decreases or increases at both the stand pipe and the drilling mud screen system, then the problem is likely down

hole and not at the drilling mud screen system 19200, 28200. If the problem is at the drilling mud screen system 19200, 28200, the drilling mud screen 1940 may be cleaned, repaired or replaced.

Optional Cementing Configuration

FIG. 10 illustrates a flow diagram for a method of using a drilling mud screen system, as discussed above. As shown in FIG. 10, the method of using a drilling mud screen system 1000 comprises stopping a drilling mud pump to stop flow of drilling mud 1005, fluidly connecting a drilling mud inlet of a drilling mud screen system downstream of an outlet to the drilling mud pump 1010, fluidly connecting a drilling mud outlet of the drilling mud screen system upstream of an outlet of a stand pipe 1015, and starting the drilling mud pump to flow drilling mud through the drilling mud screen system 1020.

In an embodiment, step 1010 comprises fluidly connecting a first drilling mud inlet of a first transducer subassembly downstream of an outlet to the drilling mud pump; and fluidly connecting a first drilling mud inlet of a drilling mud screen system downstream of an outlet to the first transducer subassembly.

In an embodiment, step 1015 comprises fluidly connecting a drilling mud outlet of the drilling mud screen system upstream of a drilling mud inlet of a gate valve, fluidly connecting a drilling mud outlet of the gate valve to a second drilling mud inlet to a second transducer subassembly, and fluidly connecting a second drilling mud outlet of the second transducer subassembly upstream of an outlet of a stand pipe.

As shown in FIG. 28, the first drilling mud inlet 28120' of the optional first transducer subassembly 28100' may be fluidly connected to, for example, an outlet of a drilling mud pump via a connection; and the first drilling mud outlet 28125' of the optional first transducer subassembly 28100' may be fluidly connected to, for example, the drilling mud inlet 28120 of the drilling mud screen system 28200 via a connection. Any suitable connection may be used for the first drilling mud inlet 28120' and the first drilling mud outlet 28125'. For example, suitable connections include, but are not limited to, pipe fittings and welds. Connections are well known in the art. In an embodiment, the first drilling mud inlet 28120' of the optional first transducer subassembly 28100' may be fluidly connected to, for example, an outlet of a drilling mud pump via a weld; and the first drilling mud outlet 28125' of the optional first transducer subassembly 28100' may be fluidly connected to the drilling mud inlet 28220 of the drilling mud screen system 28200 via a weld.

The inlet pressure to the first drilling mud inlet 28120' of the optional first transducer subassembly 28100' may be any suitable pressure. In an embodiment, the inlet pressure may be from about 7500 psi to about 10,000 psi, and any range or value or value there between.

In an embodiment, a computing device (such as a rig computer) may include a bus that directly or indirectly couples the following devices: memory, one or more processors, one or more presentation components, one or more input/output (I/O) ports, I/O components, a user interface and a power supply. The computing device may include a variety of computer-readable media. The memory may include computer-storage media in the form of volatile and/or nonvolatile memory. The presentation component(s) present data indications to a user or other device. The user interface allows the user to input/output information to/from the computing device. The one or more I/O ports may allow the computing device to be logically coupled to other devices including a transducer 28105, and other I/O com-

ponents, some of which may be built in. See e.g., FIG. 28. Examples of other I/O components include a printer, scanner, wireless device, and the like.

In an embodiment, pressure information from, for example, a pressure transducer 28105 will allow a driller to know when a drilling mud screen 1940 in a drilling mud screen system 28200 is "packing off". For example, the pressure information from the pressure transducer 28105 at the drilling mud inlet 28220 of the drilling mud screen system 28200 may be compared to, for example, pressure information from a pressure transducer on a pressure transducer for a stand pipe. If the pressure decreases at the stand pipe and the pressure increases at the drilling mud inlet 28220 of the drilling mud screen system 28200, the drilling mud screen 1940 is likely "packing off". If the pressure decreases or increases at both the stand pipe and the drilling mud screen system, then the problem is likely down hole and not at the drilling mud screen system 28200. If the problem is at the drilling mud screen system 28200, the drilling mud screen 1940 may be cleaned, repaired or replaced.

In an embodiment, the drilling mud inlet 28220 of the drilling mud screen system 28200 may be fluidly connected to, for example, the first drilling mud outlet 28125' of the optional first transducer subassembly 28100' via a connection; and a drilling mud outlet 28225 of the drilling mud screen system 28200 may be fluidly connected to, for example, the drilling mud inlet 28320 of the optional gate valve 28300 via a connection. Any suitable connection may be used for the drilling mud inlet 2820 and the drilling mud outlet 2825. For example, suitable connections include, but are not limited to, pipe fittings and welds. Connections are well known in the art. In an embodiment, the drilling mud inlet 28220 of the drilling mud screen system 28200 may be fluidly connected to, for example, the first drilling mud outlet 28120' of the optional first transducer subassembly 28100' via a weld; and the drilling mud outlet 28225 of the drilling mud screen system 28200 may be fluidly connected to, for example, the drilling mud inlet 28320 of the optional gate valve 28300 via a weld.

The inlet pressure to the drilling mud inlet 28220 of the drilling mud screen system 28200 may be any suitable pressure. In an embodiment, the inlet pressure may be from about 7500 psi to about 10,000 psi, and any range or value or value there between.

In an embodiment, the drilling mud inlet 28320 of the optional gate valve 28300 may be fluidly connected to, for example, the drilling mud outlet 28220 of the drilling mud screen system 28200 via a connection; and a drilling mud outlet 28325 of the optional gate valve 28300 may be fluidly connected to, for example, the second drilling mud inlet 28120" of the optional second transducer subassembly 28100" via a connection. Any suitable connection may be used for the drilling mud inlet 28320 and the drilling mud outlet 28325. For example, suitable connections include, but are not limited to, pipe fittings and welds. Connections are well known in the art. In an embodiment, the drilling mud inlet 28320 of the optional gate valve 28300 may be fluidly connected to, for example, the drilling mud outlet 28220 of the drilling mud screen system 28200 via a weld; and the drilling mud outlet 28225 of the optional gate valve 28300 may be fluidly connected to, for example, a second drilling mud inlet 28125" of the optional second transducer subassembly 28100" via a weld.

In an embodiment, the second drilling mud inlet 28120" of the optional second transducer subassembly 28100" may be fluidly connected to, for example, the drilling mud outlet 28325 of the optional gate valve 28300 via a connection; and

the second drilling mud outlet **28125**" of the optional second transducer subassembly **28100**" may be fluidly connected to, for example, an inlet of a vibrator hose via a connection. Any suitable connection may be used for the second drilling mud inlet **28120**" and the second drilling mud outlet **28125**". For example, suitable connections include, but are not limited to, pipe fittings and welds. Connections are well known in the art. In an embodiment, the second drilling mud inlet **28120**" of the optional second transducer subassembly **28100**" may be fluidly connected to, for example, the drilling mud outlet **28325** of the optional gate valve **28300** via a weld; and a second drilling mud outlet **28125**" of the optional second transducer subassembly **28100**" may be fluidly connected to, for example, an inlet of a vibrator hose via a weld.

In an embodiment, an operator may close an optional gate valve **28300** to isolate a drilling mud screen system **28200** (and an upstream drilling mud pump) from cement for a cementing application. The operator may pump cement through an optional low torque plug valve **28110** in an optional second transducer assembly **28100**", through a vibrator hose, through a stand pipe, through a top drive and through a casing running tool (CRT).

Method of Removing and Replacing Drilling Mud Screen for Single-Piece and Two-Piece Bodies

FIG. 11 illustrates a method of removing and replacing a drilling mud screen in a single-piece or two-piece drilling mud screen system, as discussed above. As shown in FIG. 11, the method of removing and replacing a drilling mud screen **1100** comprises providing a drilling mud screen system **1105**, stopping a drilling mud pump connected to the drilling mud screen system **1110**, opening a drilling mud screen access port and/or a union in the drilling mud screen system to remove and replace a drilling mud screen **1115**, accessing the interior of the drilling mud screen system to pull the drilling mud screen from the drilling mud screen system and to install a replacement drilling mud screen into the drilling mud screen system **1120**, closing the drilling mud screen access port and/or the union in the drilling mud screen system **1125**, and operating the drilling mud pump to produce flow of drilling mud through the drilling mud screen system **1130**.

In an embodiment, step **1115** comprises opening a drilling mud screen access port **130, 230, 330, 430** in the body **105, 205, 305, 405** of the single-piece drilling mud screen system **100, 200, 300, 400**. See also FIG. 14. In an embodiment, step **1115** comprises opening the drilling mud screen access port **630, 730** of the first body **605a, 705a** and opening a union between the first body **605a, 705a** and the second body **605b, 705b** of the two-piece drilling mud screen system **600, 700** to remove and replace the drilling mud screen **500**. See also FIGS. 19, 21, 23 & 26.

In an embodiment, step **1125** comprises closing the drilling mud screen access port **130, 230, 330, 430** in the body **105, 205, 305, 405** of the single-piece drilling mud screen system **100, 200, 300, 400**. In an embodiment, step **1125** comprises closing the drilling mud screen access port **130, 230, 330, 430** of the first body **605a, 705a** and connecting the union between the first body **605a, 705a** and the second body **605b, 705b** of the two-piece drilling mud screen system **600, 700**.

In an embodiment, step **1115** comprises opening the drilling mud screen access port **130, 230, 330, 430, 630, 730** of the drilling mud screen system **100, 200, 300, 400, 600, 700**, and step **1120** comprises using a puller/installer plate **870, 970** of a puller/installer tool **800, 900** to engage and pull the drilling mud screen **500** from the drilling mud screen system **100, 200, 300, 400, 600, 700**. In an embodiment, step

1115 comprises opening the drilling mud screen access port **130, 230, 330, 430, 630, 730** of the drilling mud screen system **100, 200, 300, 400, 600, 700**, and step **1120** comprises using the puller/installer plate **875, 975** and/or a rounded end **875, 975** of the puller/installer tool **800, 900** to install the replacement drilling mud screen **500** into the drilling mud screen system **100, 200, 300, 400, 600, 700**.

In an embodiment, step **1120** further comprises using a groove, painted line or stop plate **29110** on the shaft **825, 925** of the puller/installer tool **800, 900** to indicate when the puller/installer tool **800, 900** (and therefore, the drilling mud screen **500, 2200**) is fully inserted in the system **100, 200, 300, 400, 600, 700, 2100**.

Method of Removing and Replacing Drilling Mud Screen for Piston Body

FIG. 32 illustrates a method of removing and replacing a drilling mud screen in a four-piece drilling mud screen system, as discussed above. As shown in FIG. 32, the method of removing and replacing a drilling mud screen **3200** comprises providing a piston-style drilling mud screen system **3205**, stopping a drilling mud pump connected to the piston-style drilling mud screen system **3210**, opening a lock system in the piston-style drilling mud screen system to remove and replace a drilling mud screen **3215**, accessing the interior of the piston-style drilling mud screen system to pull the drilling mud screen from the piston-style drilling mud screen system and to install a replacement drilling mud screen into the piston-style drilling mud screen system **3220**, closing the lock system in the piston-style drilling mud screen system **3825**, and operating the drilling mud pump to produce flow of drilling mud through the piston-style drilling mud screen system **3230**.

In an embodiment, step **3215** comprises opening the lock system **30100** of the piston-style drilling mud screen system **3000**. See e.g., FIGS. 30A-30G. In an embodiment, step **3815** comprises opening the first drilling mud screen inlet **3025a** of the first body **3005a** and opening the lock system **30100** between the first body **3005a** and the second body **3005b** of the piston-style drilling mud screen system **3000** to remove and replace the drilling mud screen **500, 2200**.

In an embodiment, step **3215** comprises disengaging the first lock **30100a** in the first body **30105a** of the lock system **30100** (i.e., from the first body **3005**) and disengaging the second lock **30100b** in the second body **30105b** of the lock system **30100** (i.e., from the second body **3005**) in the piston-style drilling mud screen system **3000**. See e.g., FIGS. 30A-30B.

In an embodiment, step **3215** comprises rotating the first body **3005a** to unlatch the first assembly **30000a** (e.g., a first breech lock) and rotating the second body **3005b** to unlock the second assembly **30000b** (e.g., a second breech lock) in the piston-style drilling mud screen system **3000**. See e.g., FIGS. 30B-30C & 30G.

In an embodiment, step **3215** comprises sliding the first body **3005a** further into the lock system **30100** to fully disengage the first assembly **30000a** (e.g., the first breech lock) and sliding the second body **3005b** further into the lock system **30100** to fully disengage the second assembly **30000b** (e.g., the second breech lock) in the piston-style drilling mud screen system **3000**.

In an embodiment, step **3215** comprises lifting, lowering, rotating, pivoting, sliding or otherwise moving one or more of the first assembly **30000a**, the second assembly **30000b**, the first body **3005a**, the second body **3005b** and the lock system **30100** of the piston-style drilling mud screen system **3000** to open the lock system **30100** (and the piston-style

drilling mud screen system 3000) and to remove the drilling mud screen 500, 2200. See e.g., FIG. 30D.

In an embodiment, step 3220 comprises removing the drilling mud screen 500, 2200 from the piston-style drilling mud screen system 3000. See e.g., FIGS. 30D-30E. In an embodiment, step 3220 comprises using a puller/installer plate 870, 970 of a puller/installer tool 800, 900 to engage and pull the drilling mud screen 500, 2200 from the piston-style drilling mud screen system 3000.

In an embodiment, step 3220 comprises installing the replacement drilling mud screen 500, 2200 into the piston-style drilling mud screen system 3000. See e.g., FIG. 30D. In an embodiment, step 3220 comprises using the puller/installer plate 875, 975 and/or a rounded end 875, 975 of the puller/installer tool 800, 900 to install the replacement drilling mud screen 500, 2200 into the piston-style drilling mud screen system 3000.

In an embodiment, step 3220 further comprises using a groove, painted line or stop plate 29110 on the shaft 825, 925 of the puller/installer tool 800, 900 to indicate when the puller/installer tool 800, 900 (and therefore, the drilling mud screen 500, 2200) is fully inserted in the system 3000.

In an embodiment, step 3225 comprises lifting, lowering, rotating, pivoting, sliding or otherwise moving the one or more of the first assembly 30000a, the second assembly 30000b, the first body 3005a, the second body 3005b and the lock system 30100 of the piston-style drilling mud screen system 3000 to close the lock system 30100 and the piston-style drilling mud screen system 3000. See e.g., FIGS. 30D-30E.

In an embodiment, step 3225 comprises sliding the first body 3005a to engage the first assembly 30000a (e.g., the first breech lock) and sliding the second body 3005b to engage the second assembly 30000b (e.g., the second breech lock) of the piston-style drilling mud screen system 3000.

In an embodiment, step 3225 comprises rotating the first body 3005a to lock the first assembly 30000a (e.g., the first breech lock) and rotating the second piston 3005b to lock the second assembly 30000b (e.g., the second breech lock) in the piston-style drilling mud screen system 3000. See e.g., FIGS. 30B-30C & 30G.

In an embodiment, step 3225 comprises closing the lock system 30100 between the first body 3005a and the second body 3005b of the piston-style drilling mud screen system 3000.

In an embodiment, step 3225 comprises engaging the first lock 30100a into the first body 30105a of the lock system 30100 (and the first body 3005a) and engaging the second lock 30100b into the second body 30105b of the lock system 30100 (and the second body 3005b) in the piston-style drilling mud screen system 3000. See e.g., FIGS. 30A-30B.

Method of Removing and Replacing Drilling Mud Screen for Alternative Piston Body

FIG. 35 illustrates a method of removing and replacing a drilling mud screen in a four-piece drilling mud screen system, as discussed above. As shown in FIG. 35, the method of removing and replacing a drilling mud screen 3500 comprises providing a piston-style drilling mud screen system 3505, stopping a drilling mud pump connected to the piston-style drilling mud screen system 3510, opening a first drilling mud outlet of a first subassembly and/or a second drilling mud inlet of a second subassembly in the piston-style drilling mud screen system to remove and replace a drilling mud screen 3515, accessing the interior of the piston-style drilling mud screen system to pull the drilling mud screen from the piston-style drilling mud screen system and to install a replacement drilling mud screen into the

piston-style drilling mud screen system 3520, closing the first drilling mud outlet of the first subassembly and/or the second drilling mud inlet of the second subassembly in the piston-style drilling mud screen system 3525, and operating the drilling mud pump to produce flow of drilling mud through the piston-style drilling mud screen system 3530.

In an embodiment, step 3515 comprises opening a first drilling mud outlet 33025a of a first subassembly 33000a, 34000a and/or a second drilling mud inlet 33020b of a second subassembly 33000b, 34000b of the piston-style drilling mud screen system 3300, 3400. See e.g., FIGS. 33A-33C & 34A-34B. In an embodiment, step 3515 comprises opening the first drilling mud outlet 33025a of the first subassembly 33000a, 34000a and/or the second drilling mud inlet 33020b of the second subassembly 33000b, 34000b of the piston-style drilling mud screen system 3300, 3400 to remove and replace the drilling mud screen 500, 2200.

In an embodiment, step 3515 comprises rotating a first body 3305a, 3405a to disengage the first assembly 33000a, 34000a and/or rotating a second body 3305b, 3405b to disengage the second assembly 33000b, 34000b in the piston-style drilling mud screen system 3000. See e.g., FIGS. 33A-33C & 34A-34B.

In an embodiment, step 3515 comprises sliding the first body 3305a, 3405a further into the union system 33102, 34102 to fully disengage the first assembly 33000a, 34000a and/or sliding the second body 3305b, 3405b further into the union system 33102, 34102 to fully disengage the second assembly 33000b, 34000b in the piston-style drilling mud screen system 3000.

In an embodiment, step 3515 comprises lifting, lowering, rotating, pivoting, sliding or otherwise moving one or more of the first assembly 33000a, 34000a, the second assembly 33000b, 34000b, the first body 3305a, 3405a, the second body 3305b, 3405b and the union system 33102, 34102 of the piston-style drilling mud screen system 3300, 3400 to open the piston-style drilling mud screen system 3300, 3400 and to remove the drilling mud screen 500, 2200. See e.g., FIGS. 33A-33C & 34A-34B.

In an embodiment, step 3520 comprises removing the drilling mud screen 500, 2200 from the piston-style drilling mud screen system 3300, 3400. See e.g., FIGS. 33A-33C & 34A-34B. In an embodiment, step 3520 comprises using a puller/installer plate 870, 970 of a puller/installer tool 800, 900 to engage and pull the drilling mud screen 500, 2200 from the piston-style drilling mud screen system 3300, 3400.

In an embodiment, step 3520 comprises installing the replacement drilling mud screen 500, 2200 into the piston-style drilling mud screen system 3300, 3400. See e.g., FIGS. 33A-33C & 34A-34B. In an embodiment, step 3520 comprises using the puller/installer plate 875, 975 and/or a rounded end 875, 975 of the puller/installer tool 800, 900 to install the replacement drilling mud screen 500, 2200 into the piston-style drilling mud screen system 3300, 3400.

In an embodiment, step 3520 further comprises using a groove, painted line or stop plate 29110 on the shaft 825, 925 of the puller/installer tool 800, 900 to indicate when the puller/installer tool 800, 900 (and therefore, the drilling mud screen 500, 2200) is fully inserted in the system 3300, 3400.

In an embodiment, step 3525 comprises lifting, lowering, rotating, pivoting, sliding or otherwise moving the one or more of the first assembly 33000a, 34000a, the second assembly 33000b, 34000b, the first body 3305a, 3405a, the second body 3305b, 3405b and the union system 33102, 34102 of the piston-style drilling mud screen system 3300,

145

3400 to close the piston-style drilling mud screen system 3300, 3400. See e.g., FIGS. 33A-33C & 34A-34B.

In an embodiment, step 3525 comprises sliding the first body 3305a, 3405a to engage the first assembly 3300a, 34000a and sliding the second body 3305b, 3405b to engage the second assembly 33000b, 34000b of the piston-style drilling mud screen system 3300, 3400.

In an embodiment, step 3525 comprises rotating the first body 3305a, 3405a to fully engage the first assembly 3300a, 34000a and rotating the second body 3305b, 3405b to fully engage the second assembly 33000b, 34000b in the piston-style drilling mud screen system 3300, 3400. See e.g., FIGS. 33A-33C & 34A-34B.

In the foregoing description of certain embodiments, specific terminology has been resorted to for the sake of clarity. However, the disclosure is not intended to be limited to the specific terms so selected, and it is to be understood that each specific term includes other technical equivalents which operate in a similar manner to accomplish a similar technical purpose. Terms (e.g., "outer" and "inner," "upper" and "lower," "first" and "second," "internal" and "external," "above" and "below" and the like) are used as words of convenience to provide reference points and, as such, are not to be construed as limiting terms.

The embodiments set forth herein are presented to best explain the present invention and its practical application and to thereby enable those skilled in the art to make and utilize the invention. However, those skilled in the art will recognize that the foregoing description has been presented for the purpose of illustration and example only. The description as set forth is not intended to be exhaustive or to limit the invention to the precise form disclosed. Many modifications and variations are possible in light of the above teaching without departing from the spirit and scope of the following claims.

Also, the various embodiments described above may be implemented in conjunction with other embodiments, e.g., aspects of one embodiment may be combined with aspects of another embodiment to realize yet other embodiments. Further, each independent feature or component of any given assembly may constitute an additional embodiment.

Definitions

As used herein, the terms "a," "an," "the," and "said" mean one or more, unless the context dictates otherwise.

As used herein, the term "about" means the stated value plus or minus a margin of error plus or minus 10% if no method of measurement is indicated.

As used herein, the term "or" means "and/or" unless explicitly indicated to refer to alternatives only or if the alternatives are mutually exclusive.

As used herein, the terms "comprising," "comprises," and "comprise" are open-ended transition terms used to transition from a subject recited before the term to one or more elements recited after the term, where the element or elements listed after the transition term are not necessarily the only elements that make up the subject.

As used herein, the terms "containing," "contains," and "contain" have the same open-ended meaning as "comprising," "comprises," and "comprise," provided above.

As used herein, the terms "having," "has," and "have" have the same open-ended meaning as "comprising," "comprises," and "comprise," provided above.

As used herein, the terms "including," "includes," and "include" have the same open-ended meaning as "comprising," "comprises," and "comprise," provided above.

146

As used herein, the phrase "consisting of" is a closed transition term used to transition from a subject recited before the term to one or more material elements recited after the term, where the material element or elements listed after the transition term are the only material elements that make up the subject.

As used herein, the term "simultaneously" means occurring at the same time or about the same time, including concurrently.

INCORPORATION BY REFERENCE

All patents and patent applications, articles, reports, and other documents cited herein are fully incorporated by reference to the extent they are not inconsistent with this invention.

What is claimed is:

1. A drilling mud screen comprising:
  - (a) a first body having a first end and a second end and a first centerline;
  - (b) a filter having a first end, a second end, and openings, wherein the second end of the filter is fluidly connected to the first end of the first body via a first connection and/or a first end retaining ring;
  - (c) a first end cap fluidly connected at the first end of the filter via a second connection, wherein the filter has a filter retaining ring disposed between the first connection and the second connection;
  - (d) a drilling mud inlet at the openings of the filter; and
  - (e) a drilling mud outlet at the second end of the first body;
  - (f) wherein the first end retaining ring and/or the filter retaining ring is/are modified to reduce inside surface entry and exit angles of the drilling mud screen.
2. The drilling mud screen of claim 1, wherein the first body and/or filter is constructed from alloy steel, tool steel, or combinations thereof.
3. The drilling mud screen of claim 1, wherein the first body and/or filter is constructed from AISI 4130/75k or equivalent material, AISI 4145 or equivalent, or combinations thereof.
4. The drilling mud screen of claim 1, wherein the first body and/or filter has a hardened coating.
5. The drilling mud screen of claim 1, wherein the first body and/or filter has a Carbide coating with about 6% Cobalt binder or equivalent.
6. The drilling mud screen of claim 1, wherein the filter comprises a plurality of rods having a first end and a second end, wherein the rods are spaced a distance apart to form the openings in the filter.
7. The drilling mud screen of claim 6, wherein the rods are tapered from the first end to the second end.
8. The drilling mud screen of claim 1, wherein the filter comprises a formed sheet having drilled holes or slots spaced a distance apart to form the openings in the filter.
9. The drilling mud screen of claim 8, wherein the drilled holes or slots are drilled in offset rows or straight rows from the first end to the second end.
10. The drilling mud screen of claim 1, wherein the filter is tapered from the second end to the first end.
11. The drilling mud screen of claim 1, wherein the first end cap is a flat plate or a flat plate with holes or slots.
12. The drilling mud screen of claim 1, wherein the first end cap is an inverted cone or an inverted cone with holes or slots.
13. The drilling mud screen of claim 1, wherein the first centerline of the first body and an outer surface of the first

end cap forms a cap angle, wherein the cap angle is from about 30-degrees to about 90-degrees.

14. The drilling mud screen of claim 1, wherein the first centerline of the first body and an outer surface of the first end cap forms a cap angle, wherein the cap angle is from about 35-degrees to about 45-degrees.

15. The drilling mud screen of claim 1, wherein the entry and exit angles are from about 10 degrees to about 90-degrees.

16. The drilling mud screen of claim 1, wherein the entry and exit angles are from about 10-degrees to about 50-degrees.

17. The drilling mud screen of claim 1, wherein the entry and exit angles are about 30-degrees.

18. The drilling mud screen of claim 1, wherein the first end retaining ring and/or the filter retaining ring is constructed of alloy steel, stainless steel, or combinations thereof.

19. The drilling mud screen of claim 1, wherein the first end retaining ring and/or the filter retaining ring is constructed from AISI 4145 or equivalent, stainless steel, or combinations thereof.

20. The drilling mud screen of claim 1, wherein the first end cap is constructed of alloy steel, stainless steel, or combinations thereof.

21. The drilling mud screen of claim 1, wherein the first end cap has a hardened coating.

22. The drilling mud screen of claim 1, wherein the first end cap has a Carbide coating with about 6% Cobalt binder or equivalent material.

23. The drilling mud screen of claim 1, wherein the filter has a first section, a second section and a third section, and wherein the first section is about 20-25% longer than the second section.

24. A drilling mud screen system, comprising:

(a) a second body having a first end, a second end and a second centerline from the first end to the second end;

(b) a first drilling mud inlet having a third centerline forming a first angle with the second centerline and extending to the second centerline, wherein the first drilling mud inlet is offset from the first end of the second body and wherein the first angle is from about 20-degrees to about 120-degrees;

(c) a first drilling mud outlet at the second end of the second body;

(d) a drilling mud screen access port at the first end of the second body;

(e) a second end cap, disposed within the drilling mud access port to close and seal the drilling mud access port;

(f) the drilling mud screen of claim 1, disposed within the second body between the first drilling mud inlet and the first drilling mud outlet;

(g) wherein the first drilling mud outlet is adapted to be fluidly connected to an inlet of a vibrator hose or an inlet to a standpipe or at any point in the standpipe.

25. The drilling mud screen system of claim 24, wherein the second body comprises a third body and a fourth body, and wherein the third body is fluidly connected to the fourth body via a union.

26. The drilling mud screen system of claim 24, wherein the first body has a first portion and a second portion surrounding the filter, and wherein a first inner diameter of the first portion is larger than a second inner diameter of the second portion to provide a high flow rate of drilling mud through the filter.

27. The drilling mud screen system of claim 25, wherein one or more of the first body, the second body, the third body and the fourth body are constructed from AISI 4130/75k or equivalent material, AISI 4145 or equivalent, or combinations thereof.

28. The drilling mud screen system of claim 24, wherein the filter comprises a plurality of rods having a first end and a second end, wherein the rods are spaced a distance apart to form the openings in the filter.

29. The drilling mud screen system of claim 28, wherein the rods are tapered from the first end to the second end.

30. The drilling mud screen system of claim 24, wherein the filter comprises a formed sheet having drilled holes or slots spaced a distance apart to form the openings in the filter.

31. The drilling mud screen system of claim 24, wherein the drilled holes or slots are drilled in offset rows or straight rows from the first end to the second end.

32. The drilling mud screen system of claim 24, wherein the filter is tapered from the second end to the first end.

33. The drilling mud screen system of claim 24, wherein the first end cap is a flat plate or a flat plate with holes or slots.

34. The drilling mud screen of claim 24, wherein the first end cap is an inverted cone or an inverted cone with holes or slots.

35. The drilling mud screen system of claim 24, wherein the first centerline of the first body and an outer surface of the first end cap forms a cap angle, wherein the cap angle is from about 30-degrees to about 90-degrees.

36. The drilling mud screen system of claim 24, wherein the first centerline of the first body and an outer surface of the first end cap forms a cap angle, wherein the cap angle is from about 35-degrees to about 45-degrees.

37. The drilling mud screen system of claim 24, wherein the filter, the first end retaining ring and/or the filter retaining ring are constructed from AISI 4145 or equivalent, stainless steel or combinations thereof and/or has a hardened coating.

38. The drilling mud screen system of claim 24, wherein the filter, the first end retaining ring and/or the filter retaining ring has a Carbide coating with about 6% Cobalt binder.

39. The drilling mud screen system of claim 24, further comprising:

(a) a transducer subassembly comprising:

i. a transducer body having a first end, a second end and a third centerline from the first end to the second end;

ii. a transducer access port having a fourth centerline forming a transducer angle with the third centerline and extending to the third centerline, wherein the transducer access port is offset from the first end and wherein the transducer angle is from about 20-degrees to about 120-degrees;

iii. a drilling mud inlet at the first end of the transducer body;

iv. a drilling mud outlet at the second end of the transducer body;

v. a transducer, disposed within the transducer access port to close and seal the transducer access port; and

(b) wherein the drilling mud outlet of the transducer subassembly is fluidly connected to the first drilling mud inlet of the drilling mud screen system.

40. A method of installing a drilling mud screen system comprising the steps of:

(a) stopping a drilling mud pump to fluidly connect the drilling mud screen of claim 24 to the drilling mud pump;

149

- (b) fluidly connecting the drilling mud screen system in line with and immediately upstream or downstream of the drilling mud pump; and
- (c) operating the drilling mud pump to produce flow of drilling mud through the drilling mud screen system.

41. The method of claim **40**, wherein step b) comprises fluidly connecting a drilling mud inlet of the drilling mud screen system to a high-pressure outlet of the drilling mud pump and fluidly connecting a drilling mud outlet of the drilling mud screen system to a vibrator hose or a standpipe.

42. The method of claim **40**, wherein step b) comprises fluidly connecting a drilling mud inlet of the drilling mud screen system to a high-pressure inlet of the drilling mud pump and fluidly connecting a drilling mud outlet of the drilling mud screen system to an inlet of a vibrator hose.

43. The method of claim **40**, wherein step b) comprises fluidly connecting a drilling mud inlet of the drilling mud screen system to an outlet of a vibrator hose and a drilling mud outlet to an inlet of a standpipe.

44. The method of claim **40**, wherein step b) comprises fluidly connecting a drilling mud inlet of the drilling mud screen system to an outlet of a first portion of a standpipe and a drilling mud outlet of the drilling mud screen system to an inlet of a second portion of the standpipe.

45. The method of claim **40**, further comprising the step d) filtering or screening debris from drilling mud.

46. A method of removing and replacing a drilling mud screen comprising the steps of:

- (a) stopping a drilling mud pump connected to the drilling mud screen system of claim **24** or **26**;
- (b) opening a drilling mud screen access port and/or a union in the drilling mud screen system to remove and replace the drilling mud screen;
- (c) accessing the interior of the drilling mud screen system to pull the drilling mud screen from the drilling mud screen system and to install a replacement drilling mud screen into the drilling mud screen system;
- (d) closing the drilling mud screen access port and/or the union in the drilling mud screen system; and
- (e) operating the drilling mud pump to produce flow of drilling mud through the drilling mud screen system.

47. The method of claim **46**, wherein step b) comprises opening a drilling mud screen access port in the body of the drilling mud screen system.

48. The method of claim **47**, wherein step d) comprises closing the drilling mud screen access port of the third body and connecting the union between the third body and the fourth body of the drilling mud screen system.

49. The method of claim **46**, wherein step d) comprises closing the drilling mud screen access port in the body of the drilling mud screen system.

50. The method of claim **46**, wherein step b) comprises opening the drilling mud screen access port of the third body and opening a union between the third body and the fourth body of the drilling mud screen system to remove and replace the drilling mud screen.

51. A method of installing a drilling mud screen system comprising the steps of:

- (a) stopping a drilling mud pump;
- (b) fluidly connecting a first transducer subassembly, having a first transducer, in line with and downstream of the drilling mud pump and fluidly connecting the drilling mud screen system of claim **24** in line with and immediately downstream of the first transducer subassembly; and

150

- (c) operating the drilling mud pump to produce flow of drilling mud through the first transducer subassembly and the drilling mud screen system.

52. The method of claim **51** further comprising step (d) monitoring the first transducer of the first transducer subassembly for property information immediately upstream of the drilling mud screen system, and step (e) using the property information to determine a status of the drilling mud screen system.

53. The method of claim **51** wherein step b) comprises (b-1) fluidly connecting the first transducer subassembly, having the first transducer, in line with and downstream of the drilling mud pump, (b-2) fluidly connecting the drilling mud screen system in line with and immediately downstream of the first transducer subassembly, (b-3) fluidly connecting a gate valve in line with and immediately downstream of the drilling mud screen system, and (b-4) fluidly connecting a second transducer assembly, having a low torque plug valve, in line with and immediately downstream of the gate valve and wherein step (c) comprises operating the drilling mud pump to produce flow of drilling mud through the first transducer subassembly, the drilling mud screen system, the gate valve and the second transducer subassembly.

54. The method of claim **53** further comprising step (d) stopping the drilling mud pump, step (e) closing the gate valve to isolate the drilling mud screen system, and step (f) pumping cement through the low torque plug valve of the second transducer subassembly, a vibrator hose, a stand pipe, a top drive and a case running tool (CRT).

55. A method of installing a drilling mud screen comprising the steps of:

- (a) stopping a drilling mud pump to fluidly connect the drilling mud screen of claim **1** to the drilling mud pump;
- (b) fluidly connecting the drilling mud screen system in line with and immediately upstream or downstream of the drilling mud pump; and
- (c) operating the drilling mud pump to produce flow of drilling mud through the drilling mud screen system.

56. The method of claim **55**, wherein step b) comprises fluidly connecting a drilling mud inlet of the drilling mud screen to a high-pressure outlet of the drilling mud pump and fluidly connecting a drilling mud outlet of the drilling mud screen to a vibrator hose or a standpipe.

57. The method of claim **55**, wherein step b) comprises fluidly connecting a drilling mud inlet of the drilling mud screen to a high-pressure inlet of the drilling mud pump and fluidly connecting a drilling mud outlet of the drilling mud screen to an inlet of a vibrator hose.

58. The method of claim **55**, wherein step b) comprises fluidly connecting a drilling mud inlet of the drilling mud screen to an outlet of a vibrator hose and a drilling mud outlet of the drilling mud screen to an inlet of a standpipe.

59. The method of claim **55**, wherein step b) comprises fluidly connecting a drilling mud inlet of the drilling mud screen to an outlet of a first portion of a standpipe and a drilling mud outlet of the drilling mud screen to an inlet of a second portion of the standpipe.

60. The method of claim **55**, further comprising the step d) filtering or screening debris from drilling mud.

61. A piston-style drilling mud screen system, comprising:

- (a) a first assembly having a first end and a second end;
- (b) a first drilling mud inlet at the first end of the first assembly;

151

- (c) a first drilling mud outlet at the second end of the first assembly;
- (d) a second body having a first end and a second end;
- (e) a second drilling mud inlet at the first end of the second body, wherein the first drilling mud outlet of the first assembly is fluidly connected to the second drilling mud inlet of the second body;
- (f) a second drilling mud outlet at the second end of the second body;
- (g) a third body having a first end and a second end;
- (h) a third drilling mud inlet at the first end of the third body, wherein the second drilling mud outlet of the second body is fluidly connected to the third drilling mud inlet of the third body;
- (i) a third drilling mud outlet at the second end of the third body;
- (j) the drilling mud screen of claim 1, disposed within the second body and the third body between the first drilling mud inlet and the second drilling mud outlet; and
- (k) a union system, comprising:
  - i. a fourth body having a first inlet at a first end and a first outlet at second end;
  - ii. a fifth body having a second inlet at a first end and a second outlet at a second end; and
  - iii. a sixth body having a first and second end;
  - iv. wherein the second end of the second body is disposed through the first end of the sixth body such that a portion of the fourth body is disposed between the second end of the third body and a portion of the first end of the sixth body;
  - v. wherein the first end of the third body is disposed through the second end of the sixth body such that a portion of the fifth body is disposed between the first end of the third body and a portion of the second end of the sixth body;
  - (l) a second assembly having a first end and a second end;
  - (m) a fourth drilling mud inlet at the first end of the second assembly, wherein the third drilling mud outlet of the third body is fluidly connected to the fourth drilling mud inlet of the second assembly; and
  - (n) a fourth drilling mud outlet at the second end of the second assembly.

62. The drilling mud screen system of claim 61, wherein the second end of the second body is modified to reduce an inside surface exit angle to transition from a first inner diameter of the second body to a second inner diameter of the sixth body.

63. The drilling mud screen system of claim 62, wherein the exit angle is from about 10-degrees to about 90-degrees.

64. The drilling mud screen system of claim 62, wherein the exit angle is about 40-degrees.

65. The drilling mud screen system of claim 61, wherein the first end of the third body is modified to reduce an inside surface entry angle to transition from the second inner diameter of the sixth body to a third inner diameter of the third body.

66. The drilling mud screen system of claim 65, wherein the entry angle is from about 10-degrees to about 90-degrees.

67. The drilling mud screen system of claim 65, wherein the entry angle is about 30-degrees.

68. The drilling mud screen system of claim 61, wherein the second end of the fourth body and the first end of the sixth body form a first union; and the second end of the sixth body and the first end of the fifth body form a second union.

152

- 69.** The drilling mud screen system of claim 61, wherein the first drilling mud outlet of the first assembly is fluidly connected to the second drilling mud inlet of the first body via a connection.
- 70.** The drilling mud screen system of claim 61, wherein the third drilling mud outlet of the second body is fluidly connected to the fourth drilling mud inlet of the second assembly via a connection.
- 71.** The drilling mud screen system of claim 61, wherein the first outlet of the fourth body is connected to the second inlet of the fifth body via a connection.
- 72.** The drilling mud screen system of claim 61, wherein the sixth body of the union system is capable of receiving a portion of the second body when the first drilling mud outlet of the first subassembly is opened.
- 73.** The drilling mud screen system of claim 61, wherein the sixth body of the union system is capable of receiving a portion of the third body when the second drilling mud inlet of the second subassembly is opened.
- 74.** The drilling mud screen system of claim 61, further comprising:
  - (a) a skid comprising:
    - i. a base;
    - ii. a first support having a first end and a second end, wherein the first end of the first support is attached to the base and wherein the second end of the first support is attached to the first assembly;
    - iii. a second support having a first end and a second end, wherein the first end of the second support is attached to the base and wherein the second end of the second support is attached to the second assembly; and
    - iv. a third support having a first end and a second end, wherein the first end of the third support is attached to the base and wherein the second end of the third support is attached to the union system.
- 75.** The drilling mud screen system of claim 74, wherein one or more of the first support, the second support and the third support is capable of being lowered, pivoted, raised, rotated or any combination thereof.
- 76.** The drilling mud screen system of claim 74, wherein one or more of the first support, the second support and the third support is capable of being lowered, pivoted, raised, rotated or any combination thereof via a connection, coupling and/or extension.
- 77.** The drilling mud screen system of claim 74, wherein one or more of the first support, the second support and the third support is capable of being automatically lowered, pivoted, raised and/or rotated.
- 78.** The drilling mud screen system of claim 74, wherein one or more of the first support, the second support and the third support is capable of being manually lowered, pivoted, raised and/or rotated.
- 79.** The drilling mud screen system of claim 61, wherein one or more of the first assembly, the second assembly, the second body, the third body, the fourth body, the fifth body and the sixth body are constructed from AISI 4130/75k or equivalent material, AISI 4145 or equivalent, or combinations thereof.
- 80.** The drilling mud screen system of claim 61, wherein the drilling mud screen is constructed from AISI 4145 or equivalent, stainless steel or combinations thereof.
- 81.** The drilling mud screen system of claim 61, wherein the drilling mud screen has a hardened coating.

153

82. The drilling mud screen system of claim 61, further comprising

- (a) a transducer subassembly comprising:
  - i. a transducer body having a first end, a second end and a first centerline from the first end to the second end;
  - ii. a transducer access port having a second centerline forming a transducer angle with the first centerline and extending to the first centerline, wherein the transducer access port is offset from the first end and wherein the transducer angle is from about 20-degrees to about 120-degrees;
  - iii. a drilling mud inlet at the first end of the transducer body;
  - iv. a drilling mud outlet at the second end of the transducer body;
  - v. a transducer, disposed within the transducer access port to close and seal the transducer access port; and
- (b) wherein the drilling mud outlet of the transducer subassembly is fluidly connected to the first drilling mud inlet of the piston-style drilling mud screen system.

83. The drilling mud screen system of claim 82, wherein the drilling mud outlet of the transducer subassembly is fluidly connected to the first drilling mud inlet of the piston-style drilling mud screen system via a cross-over connection.

84. A method of removing and replacing a drilling mud screen in a piston-style drilling mud screen system comprising the steps:

- (a) stopping a drilling mud pump connected to the piston-style drilling mud screen system of claim 61;
- (b) opening the first drilling mud outlet of the first subassembly and/or the second drilling mud inlet of the second subassembly in the piston-style drilling mud screen system to remove and replace a drilling mud screen;
- (c) accessing the interior of the piston-style drilling mud screen system to pull the drilling mud screen from the piston-style drilling mud screen system and to install a replacement drilling mud screen into the piston-style drilling mud screen system;
- (d) closing the first drilling mud outlet of the first subassembly and/or the second drilling mud inlet of the second subassembly in the piston-style drilling mud screen system; and
- (e) operating the drilling mud pump to produce flow of drilling mud through the piston-style drilling mud screen system.

85. The method of claim 84, wherein step (b) comprises:

- (b-1) rotating the second body to disengage the first assembly and/or rotating the third body to disengage the second assembly; and

- (b-2) sliding the second body further into the union system to fully disengage the first assembly and/or sliding the third body into the union system to fully disengage the second assembly.

86. The method of claim 85, where step (b) further comprises:

- (b-3) lifting, lowering, pivoting, rotating, sliding or otherwise moving one or more of the first assembly, the

154

second assembly, the union system and any combination thereof to open the piston-style drilling mud screen system to remove the drilling mud screen.

87. The method of claim 84, wherein step (d) comprises:

- (d-1) lifting, lowering, pivoting, rotating, sliding or otherwise moving one or more of a first assembly, a second assembly, the union system and any combination thereof to close the piston-style drilling mud screen system;

- (d-2) sliding the second body to engage the first assembly and/or sliding the third body to engage the second body; and

- (d-3) rotating the second body to fully engage the first assembly and/or rotating the third body to fully engage the second assembly.

88. A method of installing a piston-style drilling mud screen system comprising the steps of:

- (a) stopping a drilling mud pump;
- (b) fluidly connecting a first transducer subassembly, having a first transducer, in line with and downstream of the drilling mud pump and fluidly connecting the piston-style drilling mud screen system of claim 61 in line with and immediately downstream of the first transducer subassembly; and
- (c) operating the drilling mud pump to produce flow of drilling mud through the first transducer subassembly and the piston-style drilling mud screen system.

89. The method of claim 88 further comprising step (d) monitoring the transducer of the first transducer subassembly for property information immediately upstream of the piston-style drilling mud screen system and step (e) using the property information to determine a status of the piston-style drilling mud screen system.

90. The method of claim 88 wherein step (b) comprises:

- (b-1) fluidly connecting the first transducer subassembly, having the first transducer, in line with and downstream of the drilling mud pump and fluidly connecting the piston-style drilling mud screen system of claim 61 in line with and immediately downstream of the first transducer subassembly;

- (b-2) fluidly connecting a gate valve in line with and immediately downstream of the piston-style drilling mud screen system; and

- (b-3) fluidly connecting a second transducer assembly, having a low torque plug valve, in line with and immediately downstream of the gate valve; and

wherein step (c) comprises operating the drilling mud pump to produce flow of drilling mud through the first transducer subassembly, the piston-style drilling mud screen system, the gate valve and the second transducer subassembly.

91. The method of claim 88 further comprising step (d) stopping the drilling mud pump, step (e) closing the gate valve to isolate the piston-style drilling mud screen system, and step (f) pumping cement through the low torque plug valve of the second transducer subassembly, a vibrator hose, a stand pipe, a top drive and a case running tool (CRT).
